(57) **ABSTRACT**

A developing device that can be mounted to and dismounted from a mounting and dismounting section provided in an image forming apparatus main unit, the developing device includes: a developing device main unit; a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in the longitudinal direction of the developing device main unit in such a manner that its relative position to the developing device main unit can be changed; and an element capable of communication in a noncontacting manner with the image forming apparatus main unit side when the developing device is mounted to the mounting and dismounting section, the element being provided at the one end side in the longitudinal direction of the developing device main unit.

DEVELOPING DEVICE, IMAGE FORMING APPARATUS, IMAGE FORMING SYSTEM, CARTRIDGE, DEVELOPING UNIT AND PHOTOCONDUCTOR UNIT

TECHNICAL FIELD

The present invention relates to developing devices, image forming apparatuses, image forming systems, cartridges, developing units and photoconductor units.

BACKGROUND ART

Image forming apparatuses such as laser beam printers are well known. Such image forming apparatuses include, for example, an image bearing member for bearing a latent image, and a developing device for developing the latent image borne on the image bearing member with a developer, wherein the developing device can be mounted to and dismounted from a mounting and dismounting section provided in the image forming apparatus main unit. When an image signal or the like is sent from an external device, such as a host computer, to this image forming apparatus, the developing device is positioned at the developing position opposite to the image bearing member, a developer image is formed by developing the latent image borne on the image bearing member with the developer inside the developing device, and an image is ultimately formed on the medium by transferring this developer image onto the medium.

Such a developing device has a positioning member for positioning a developing device main unit with respect to the mounting and dismounting section by engaging with the mounting and dismounting section when being mounted to the mounting and dismounting section. This positioning member is fixed to one end, with respect to the longitudinal direction, of the developing device main unit. Moreover, the developing device includes an element that can communicate in a noncontacting manner with the image forming apparatus main unit side when the developing device is mounted to the mounting and dismounting section.

Furthermore, there are developing devices that have a coupling member that is attached to the other end, in longitudinal direction, of the developing device main unit and that is coupled to the mounting and dismounting section when the developing device is mounted to the mounting and dismounting section. This coupling member is attached in such a manner that its relative position to the developing device main unit can be changed, for the purpose of setting the spacing between the image bearing member and the developing device when the developing device develops the latent image borne on the image bearing member to a desired spacing, even when the image bearing member is attached in a slanted manner with respect to the image forming apparatus main unit (see publication of WO 03/098355).

Now, in this developing device, the coupling member that is coupled to the mounting and dismounting section when the developing device is mounted to the mounting and dismounting section is attached to the developing device main unit in such a manner that its relative position to the developing device main unit is variable, so that depending on the position where the element is attached to the developing device main unit, there is the possibility that the distance between the element and the image forming apparatus main unit changes considerably as this relative position changes. In this case, there is the risk that the element cannot communicate properly with the image forming apparatus main unit side.

Also, image forming apparatuses that make recordings by electrophotography, in which an electrostatic latent image on the surface of a carrying member fabricated by a photoconductor is exposed and formed, are known, and in such image forming apparatuses, the toner image on the surface of the carrying member, obtained by developing this electrostatic latent image with toner, is transferred to a recording medium, such as recording paper, to accomplish image formation. This toner image is developed with toner by rotating a developing roller facing the surface of the carrying member and letting toner on the outer circumferential surface of that roller selectively transfer to the electrostatic latent image on the surface of the carrying member and adhere to it.

Among such image forming apparatuses employing recording by electrophotography, there are also apparatuses configured such that developing cartridges (developing containers), which include not only the developing roller facing the carrying member but also a container containing the toner, can be mounted removably, and a plurality of such developing cartridges can be accommodated in a developing rotary unit. In such an image forming apparatus, the developing cartridge at the developing position in which the developing roller faces the carrying member can be switched by rotating this developing rotary unit around a rotation shaft.

Thus, by devising such an image forming apparatus such that developing cartridges containing yellow (Y), magenta (M), cyan (C) and black (K) toner, respectively, serving as the developing cartridges adhering toner to the carrying member surface can be accommodated by (mounted to) the developing rotary unit, it is possible to form a color image in which toner of various colors is superimposed on each other by successively switching the developing cartridges. Needless to say, with this configuration, it is also possible to form a single-color image with toner of one color, for example a black-and-white monochrome image (referred to simply as monochrome image in the following) obtained with black (K) toner.

Here, in such an image forming apparatus, toner development is performed while both the carrying member and the developing roller rotate, so that it is difficult to transfer all of the toner on the circumferential surface of the developing roller to the carrying member or recover it inside the developing cartridge. Therefore, since the toner is a fine powder, it may scatter/drift from the developing position facing the carrying member to the surroundings and accumulate, and that it pollutes the recording paper or the like. For this reason, there are cases in which image forming apparatuses employing electrophotography are provided with an exhaust duct that provides suction in the vicinity of this developing position and exhausts.

Moreover, with an image forming apparatus provided with such a developing rotary unit, it is possible to freely choose, for example, the toner color of each of a plurality of the developing cartridges individually, and since also the remaining toner amount differs, it has been proposed to place a memory (storage element) storing and holding various kinds of information on each developing cartridge (see for example Patent Document 1). In this case, by accessing the memories in the developing cartridges, it is possible to confirm the type of the developing cartridge by reading out the information in the memory, and to associate various kinds of information with the developing cartridges themselves, by rewriting for example the remaining amount of toner contained in them (see WO 03/098356).

However, in such image forming apparatuses, devices generating heat, such as a device exposing/forming the electrostatic latent image on the carrying member surface or the

fixing device that fixes the toner image by applying pressure and heat to the recording paper onto which the toner image has been transferred, are arranged inside the apparatus main unit. Therefore, when the memories placed on the developing cartridges are subjected to this thermal influence, then there is the risk that the storage elements placed on the developing cartridges of this image forming apparatus are not only adversely affected, but in the worst case errors may occur during the reading and writing (rewriting) of storage information in those memories.

Furthermore, if the stored information is read out and written by communication in a noncontacting manner with the memories of the developing cartridges from the apparatus main unit side, then there is similarly not only the risk that a communication controller is adversely affected by the heat inside the apparatus main unit, but also that, in the worst case, the communication performance drops.

Moreover, it is necessary to establish a connection, to the memories on the outer surface of the rotating developing cartridges accommodated in the developing rotary unit, that allows the exchange of various kinds of information (signals).

On the other hand, as shown in FIG. 30(a), in this image forming apparatus, a suction opening 2161a of an exhaust duct 2160 provides suction near a developing position where a developing roller 2014a of a developing cartridge 2014 faces a carrying member 2012, but as shown in FIG. 30(b), there may be a case where the rotation of a developing rotary unit 2015 for switching the developing cartridge 2014 begins before all of the drifting toner t is sucked away, and the drifting toner t moves along the outer surface of the developing cartridge 2014 before it is sucked away. This problem becomes more significant the more the processing speed of the image formation increases, since the time for which the developing cartridge 2014 stops after the developing is finished becomes shorter.

Typically, a memory 2141 placed on the outer surface of this developing cartridge 2014 is placed in the middle with respect to the main scanning direction (the axial direction of the developing roller 2014a), as described in the above-noted Document 1. Moreover, the suction opening 2161 of the exhaust duct 2160 is formed such that it covers the entire axial length of the developing roller 2014a facing the carrying member 2012, so as to suck in the drifting toner t. Therefore, the memory 2141 on the outer surface of the developing cartridge 2014 is moved within a region where it comes into contact with the drifting toner t (the region where it passes near the suction opening 2161).

However, if the communication section communicating with the apparatus main unit side in order to exchange storage information inside the memory 2141 on the side of the developing cartridge 2014 is polluted through contact with drifting toner t, there is the risk of communication faults, regardless of whether this communication section is connected in a contacting manner or in a noncontacting manner. When accessing the memory 2141 in such a state of connection fault, there is the risk that errors occur in the reading or writing (rewriting) of the information stored in the memory 2141. Moreover, when the surface of the memory 2141 is polluted, then there is the possibility that for example the outer surface of the memory 2141 is adversely affected by adhering substances.

Moreover, devices generating heat during operation (heat sources) are placed inside the apparatus main unit, for example an exposing unit that forms the electrostatic latent image by exposing/scanning the carrying member surface is disposed in a lower part of the apparatus main unit. In the course of the faster speeds attained in recent years, the amount of heat generated by the exposing unit, which is a

heat-generating member, has increased, and in the course of miniaturization the various parts of the apparatus are laid out at ever closer positions.

Therefore, if the developing cartridge is laid out such that it rotates at a position close to the exposing unit, then it may stop its rotation at a position facing this exposing unit. In this situation, when for example the memory on the outer surface of the developing cartridge or the communication controller is subjected to the thermal influence of the exposing unit, whose temperature has increased, then it is at least adversely affected, and in the worst case, there is the risk that errors may occur in the reading and writing (rewriting) of information stored in this memory, and the communication performance drops.

Also, image forming apparatuses that make recordings by electrophotography, in which an electrostatic latent image on the surface of a carrying member fabricated by a photoconductor is exposed and formed, are known, and in such image forming apparatuses, the toner image on the surface of the carrying member, obtained by developing this electrostatic latent image with toner, is transferred to a recording medium, such as recording paper, to accomplish image formation. This toner image is developed with toner by rotating a developing roller facing the surface of the carrying member and letting toner on the outer circumferential surface of that roller selectively transfer to the electrostatic latent image on the surface of the carrying member and adhere to it.

In such image forming apparatuses employing electrophotography, there are also apparatuses configured such that developing cartridges (developing containers), which include not only the developing roller facing the carrying member but also a container containing the toner, can be mounted removably, and a plurality of such developing cartridges can be accommodated in a developing rotary unit. In such an image forming apparatus, the developing cartridge at the developing position in which the developing roller faces the carrying member can be switched by rotating this developing rotary unit around a rotation shaft.

Thus, by devising such an image forming apparatus such that developing cartridges containing yellow (Y), magenta (M), cyan (C) and black (K) toner, respectively, serving as the developing cartridges adhering toner to the carrying member surface can be accommodated by (mounted to) the developing rotary unit, it is possible to form a color image in which toner of various colors is superimposed on each other by successively switching the developing cartridges. Needless to say, with this configuration, it is also possible to form a single-color image with toner of one color, for example a black-and-white monochrome image (referred to simply as monochrome image in the following) obtained with black (K) toner.

Moreover, with image forming apparatuses including such a developing rotary unit, it is possible to freely select for example the toner color of each of a plurality of the cartridges individually, and since also the remaining toner amount differs, it has been proposed to place a memory (storage element) storing and holding various kinds of information on each developing cartridge, and use the memory to read or write information stored in the memory by communication in a noncontacting manner via antennas (see publication of WO 03/098356). In this case, by accessing the memories in the developing cartridges, it is possible to confirm the type of the developing cartridge by reading out the information in the memories, and to associate various kinds of information with the developing cartridges themselves, by rewriting for example the remaining amount of toner contained in them.

However, in such conventional image forming apparatuses using recording by electrophotography, the toner is transferred using a potential difference, when developing the electrostatic latent image formed on the surface of the carrying member by adhering toner to it. Therefore, in this image forming apparatus, it is necessary to charge one or both of the members passing on or receiving the toner to a high voltage, and there is the possibility that noise is emitted during the charging or from the charged member. Therefore, when this noise unnecessarily enters for example an antenna performing communication in a noncontacting manner to rewrite the information stored in the memory placed on the developing cartridge, then there is the risk that the information stored in the memory is deleted or otherwise becomes inaccurate.

Moreover, image forming apparatuses such as laser beam printers are well known. Such image forming apparatuses include, for example, a photoconductor for carrying a latent image, and a developing device that develops the latent image borne on the photoconductor by the developer and that can be mounted or dismounted with respect to the image forming apparatus main unit. When image signals or the like are sent from an external device, such as a host computer, the developing device is positioned in the developing position at which it faces the photoconductor, the latent image borne on the photoconductor is turned into a developer image by developing it with the developer inside the developing device, this developer image is transferred onto a medium, and finally an image is formed on the medium.

Moreover, there are developing devices including an element that can perform wireless communication with an antenna with which the image forming apparatus main unit is provided, facing that antenna across a gap in a state in which the developing device is mounted to the image forming apparatus main unit (see publication of WO 03/087952).

Now, when the element and the antenna perform wireless communication, electromagnetic waves are propagated through the gap between the element and the antenna. Therefore, when too much noise intrudes into this gap from the outside, suitable wireless communication is obstructed. Consequently, there is a need for a way to reduce the amount of noise intruding into that gap.

Moreover, as a cartridge mounted to a laser beam printer or the like serving as an image forming apparatus, a developing device containing a developer is known, for example. This developing device is provided with a memory unit for storing a toner consumption amount or a remaining toner amount, for example. This memory unit includes an IC memory and an antenna for communicating contactlessly with the printer main unit in a position in which it faces that antenna, which is provided on the main unit side, when the developing device is mounted to the printer main unit (see WO 03/098356). Moreover, in order to ensure favorable communication conditions between the memory unit and a communication unit, the memory unit is provided at an outer circumference of the cartridge, so as to come close to the communication unit.

Now, the developing device is mounted in the printer by passing it from outside the printer through a frame of the printer or the like. Since the frame of the printer needs to ensure rigidity and prevent the intrusion of light to the region near the photoconductive drum, also the opening for mounting the developing containers is formed slightly larger than the outer shape of the process cartridges. Therefore, when a developing device is held by a user or the like and mounted to the printer, the developing device is in an instable state until a portion of the developing device is supported by the printer, and there is the risk that the IC memory of the memory unit provided on the outer circumference of the developing device

is damaged by inadvertently bumping it into the frame of the printer or the like. Therefore, there was the problem that the user, for example, has to insert the developing device carefully into the printer.

Moreover, as a cartridge mounted to a laser beam printer or the like serving as an image forming apparatus, a process cartridge provided with a photoconductive drum or a developing roller is known, for example. This process cartridge is provided with a memory unit for storing the time that the photoconductive drum has been used, for example. This memory unit includes an IC memory and an antenna for communicating contactlessly in a position in which it faces a communication unit provided on the main unit side when the process cartridge is mounted to the printer main unit (see JP-A-H11-348375).

In such an image forming apparatus, there is the problem that favorable communication is not possible when the memory unit and the communication unit are not arranged at suitable positions, in order to perform communication in a noncontacting manner between the memory unit and the communication unit.

Moreover, for example, a developing device mounted to a laser beam printer or the like is known as a developing device containing a developer. This developing container is provided with a memory unit for storing a toner consumption amount or a remaining toner amount, for example. This memory unit includes an IC memory and an antenna for communicating contactlessly with the printer main unit by electromagnetic induction, in a position in which it faces an antenna provided on the main unit side when the developing container is mounted to the printer main unit (see publication of WO 03/087952). Moreover, in order to ensure favorable communication conditions between the memory unit and a communication unit, the memory unit is provided at an outer circumference of the developing device containing the developer, so that the memory unit comes close to the communication unit.

As the developer used in the laser beam printer, there are developers in which a magnetic material, that is, a material having conductivity, is included, as in developers in which for example a non-magnetic toner and a magnetic carrier are mixed together. When such a developer including a magnetic material is contained inside the developing container, then there is a case where it contacts the inner circumferential surface at a position where the memory unit is provided on the outer circumference side, so that the magnetic material is contained there and the magnetic material adheres to this inner circumferential surface.

However, since the memory unit and the communication unit communicate by electromagnetic induction, when a magnetic material is present at the inner circumferential surface of the developing container where the memory unit is attached, then there is the problem that when the magnetic flux generated on one side passes through the magnetic material, eddy currents flow in the magnetic material with the magnetic flux at the axial center, the propagated waves are attenuated considerably, and communication may not be possible.

Moreover, as a cartridge mounted to a laser beam printer or the like serving as an image forming apparatus, process cartridges provided with a photoconductive drum or a developing roller are known, for example. Such a process cartridge is provided with a memory unit for storing the time that the photoconductive drum has been used, for example. This memory unit includes an element and an antenna for communicating contactlessly in a position in which it faces the com-

munication antenna, which is provided on the printer side, when the process cartridge is mounted inside the printer (see JP-A-H11-348375).

In such an image forming apparatus, the outer circumference is covered by a cover or the like, and the temperature inside the apparatus increases due to heat generated by electric components during the image forming operation. At this time, also the temperature of the antenna for communication, which is provided on the printer side, may increase. In the above-described case, in which the memory unit communicates contactlessly with the printer, there is the problem that, depending on the antenna characteristics, there is the risk that favorable communication between the memory unit and the printer may not be possible when the temperature of the antenna provided on the printer side increases.

Moreover, image forming apparatuses such as laser beam printers are already well known. Such image forming apparatus include, for example, a photoconductor for carrying a latent image, and a developing unit that develops the latent image borne on the photoconductor with a developer and that can be mounted or dismounted with respect to the image forming apparatus main unit. When image signals or the like are sent from an external device, such as a host computer, the developing unit is positioned in the developing position at which it faces the photoconductor, the latent image borne on the photoconductor is turned into a developer image by developing it with the developer inside the developing unit, this developer image is transferred onto a medium, and finally an image is formed on the medium.

Moreover, among such developing units, there are developing units that have a memory unit including a memory, and onto which a label on which information relating to the developing unit is written is stuck (see publication of WO 03/098356).

Moreover, in determining where to attach the memory unit to the developing unit, the prevention of damage to the memory unit needs to be taken into consideration. Since the developing unit is mounted and dismounted by a user or the like, it is necessary to devise measures effectively preventing damage to the memory unit by the user touching the memory unit or the memory unit touching other parts of the image forming apparatus during the mounting or dismounting.

As an approach to solve this problem, the approach of embedding the memory unit in the developing unit and covering it with a lid is known. However in this case, it is necessary to provide a separate lid, so that the number of parts increases.

DISCLOSURE OF INVENTION

Accordingly, in view of the aforementioned problems, it is an object of the present invention to realize a developing device which can perform suitable communication with the image forming apparatus main unit side.

A main first invention for solving the above-noted problem is a developing device that can be mounted to and dismounted from a mounting and dismounting section provided in an image forming apparatus main unit, the developing device including: a developing device main unit; a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted

to the mounting and dismounting section, the coupling member being attached to the other end side in the longitudinal direction of the developing device main unit in such a manner that its relative position to the developing device main unit can be changed; and an element capable of communication in a noncontacting manner with the image forming apparatus main unit side when the developing device is mounted to the mounting and dismounting section, the element being provided at the one end side in the longitudinal direction of the developing device main unit.

It is another object of the present invention to provide an image forming apparatus with which the storage element of each developing cartridge can be accessed and utilized accurately and quickly, because it is as little as possible susceptible to thermal influences inside the apparatus main unit, and no errors occur in the processing of stored information and there is no drop in communication performance.

A main second invention for attaining the above-noted object is an image forming apparatus including: a bearing member for bearing an electrostatic latent image; a developing cartridge for developing the electrostatic latent image by selectively adhering a toner to the electrostatic latent image on a surface of the bearing member; a developing rotary unit provided in an apparatus main unit, that accommodates a plurality of the developing cartridges that can be inserted and removed around a rotation shaft, and lets one of the developing cartridges oppose the surface of the bearing member by rotating around the rotation shaft; and a storage element that stores and holds information relating to the developing cartridge, the storage element being provided at a position on an outer surface of the developing cartridge where its distance to an external cover of the apparatus main unit is shortest when the memory element communicates with the apparatus main unit after having been stopped in that stop position of the plurality of stop positions, at which the developing cartridge stops when being rotatively moved by the developing rotary unit, in which the outer surface of the developing cartridge is closest to the external cover.

It is another object of the present invention to provide an image forming apparatus with which the storage element of each developing cartridge can be accessed and utilized accurately, because there is as little pollution with toner of a communication section for accessing the storage element and the storage element itself as possible, and there are no errors in the processing of the stored information.

A main third invention for attaining this object is an image forming apparatus including:

a bearing member for bearing an electrostatic latent image; a developing cartridge for developing the electrostatic latent image by selectively adhering toner to the electrostatic latent image on a surface of the bearing member;

a developing rotary unit provided in an apparatus main unit, that accommodates a plurality of the developing cartridges that can be inserted and removed around a rotation shaft, and lets one of the developing cartridges oppose the surface of the bearing member by rotating around the rotation shaft;

a duct having a suction opening for sucking a toner that drifts in a vicinity of a developing position at which the developing cartridge adheres a toner to the electrostatic latent image on the surface of the developing member, by providing suction near the developing position;

a storage element for storing and holding information relating to the developing cartridge; and

communication sections for letting the apparatus main unit and the storage element communicate with each other, the communication sections being placed to the outside, in a

direction along the rotation shaft, of a part of the duct where the suction opening is formed.

It is another object of the present invention to provide an image forming apparatus which is as little susceptible as possible to the thermal influence of heat-generating members when the rotation of the developing cartridge is stopped, so that there are no errors and no drop in communication performance during the processing of storage information in the storage element of each of the developing cartridges, and this storage information can be utilized with high reliability.

A main fourth invention for attaining this object is an image forming apparatus that forms an image by transferring a toner image on a bearing member surface onto a recording medium and fixing the toner image, the image forming apparatus including:

a bearing member that bears a toner image made by forming an electrostatic latent image based on image data on a surface and developing that electrostatic latent image;

an exposing unit that forms the electrostatic latent image based on the image data by selectively scanning and exposing the bearing member surface;

a developing cartridge that develops the electrostatic latent image by selectively adhering toner to the electrostatic latent image on the bearing member surface;

a developing rotary unit that accommodates a plurality of the developing cartridges that can be inserted and removed around a rotation shaft and lets one of the developing cartridges face the bearing member surface by rotating around the rotation shaft; and

a controller that controls the driving of various sections of the apparatus, including the bearing member and the developing cartridge, based on received image data and various kinds of information;

wherein a storage element storing and holding information relating to the developing cartridge is placed on an outer surface of the developing cartridge, and a communication means is provided that performs communication by reading out at least information inside the storage element as information to be processed by the controller; and

wherein the storage element is arranged outside a position facing a heat-generating member when the rotation of the developing cartridge is stopped.

It is another object of the present invention to provide an image forming apparatus in which the storage element placed on each of the developing cartridges is not influenced by the presence of a high-voltage member inside the apparatus main unit, so that the storage information inside the storage element can be utilized with high reliability.

A main fifth invention for attaining this object is an image forming apparatus that forms an image by transferring a toner image on a bearing member surface onto a recording medium and fixing the toner image, the image forming apparatus including: a bearing member that bears a toner image made by forming an electrostatic latent image based on image data on a surface and developing that electrostatic latent image; a developing cartridge that develops the electrostatic latent image by selectively adhering toner to the electrostatic latent image on the bearing member surface; a developing rotary unit that accommodates a plurality of the developing cartridges that can be inserted or removed around a rotation shaft and lets one of the developing cartridges face the bearing member surface by rotating around the rotation shaft; a controller that controls the driving of various sections of the apparatus, including the bearing member and the developing cartridge, based on received image data and various kinds of information;

the image forming apparatus further including:

a storage element that stores and holds information relating to the developing cartridge, placed on an outer surface of the developing cartridge, and a communication means that has a function of performing communication in a noncontacting manner, with antennas being placed at positions where the developing cartridge side can face the apparatus main unit side, and that performs communication in a noncontacting manner by reading out at least information inside the storage element as information processed by the controller;

wherein a blocking member is placed between a high-voltage member, which takes on a voltage equal or greater than that which is necessary for the adherence and transfer of a toner, and a rotation trajectory of the storage element on the outer surface of the developing cartridge, the blocking member limiting the influence that noise caused by the high-voltage member has on the storage element.

It is a further object of the present invention to realize a developing device, an image forming apparatus and an image forming system with which the amount of noise that intrudes 20 the gap between the element and the antenna when the element and the antenna communicate wirelessly can be reduced.

A main sixth invention for attaining this object is a developing device that can be mounted to and dismounted from an image forming apparatus main unit, the developing device including:

an element that, when the developing device is mounted to the image forming apparatus main unit, faces, across a gap, an antenna provided to the image forming apparatus main unit, and is capable of wireless communication with the antenna; and

a metal plate, at least a portion of which is positioned to the outer side of the gap and at a position corresponding to the gap in a direction from the element toward the antenna, when the developing device is mounted to the image forming apparatus main unit and the element performs wireless communication with the antenna.

It is a further object of the present invention to realize a cartridge that can be easily mounted to an image forming apparatus, as well as a developing device, an image forming apparatus and an image forming system.

A main seventh invention for attaining this object is (c) a cartridge including:

(a) a communication unit including:
a base;
an antenna supported by the base; and
an element supported by the base, the element being for communication via the antenna; and

(b) a housing by which the communication unit is supported with the element being positioned on an upstream side of the base, with respect to a mounting direction in which it is mounted to the image forming apparatus main unit.

It is a further object of the present invention to realize an image forming apparatus with which favorable communication can be achieved between the image forming apparatus main unit and the cartridge.

A main eighth invention for attaining this object is (d) an image forming apparatus including: (a) a mounting section that is to be mounted with a cartridge provided with an element unit having a first antenna and an element; (b) an antenna unit including a second antenna for communicating with the first antenna, the antenna unit being arranged at a position that is spaced by a predetermined distance L from the first antenna of the cartridge mounted into the mounting section; and (c) a communication region in which no conductive members are present besides the element unit, the antenna

11

unit and a wire connected to the antenna unit, within a distance of L from the first antenna and within a distance of L from the second antenna.

It is a further object of the present invention to realize a developing device with which favorable communication is possible, even when a developer containing a magnetic material is contained in the developing device.

A main ninth invention for attaining this object is a developing device including:

a developing container containing a developer including a magnetic material;

a container-side antenna provided at the developing container, that is for communicating in a contactless manner, when mounted to an apparatus main unit, with a main unit-side antenna of the apparatus main unit; and

an intrusion prevention section for preventing intrusion of the developer into a predetermined region between the container-side antenna and the developer.

It is a further object of the present invention to realize an image forming apparatus with which favorable communication between the image forming apparatus and the cartridge can be accomplished even when the temperature inside the apparatus rises.

A main tenth invention for attaining this object is (d) an image forming apparatus including:

(a) a mounting section that is to be mounted with a cartridge so that it can be mounted and dismounted;

(b) a duct serving as an air passageway within an apparatus including the mounting section; and

(c) a second antenna provided to the duct, the second antenna being for communicating with an element provided with the cartridge, via a first antenna provided to the cartridge.

It is a further object of the present invention to effectively prevent the destruction of the memory unit without increasing the number of parts.

A main eleventh invention for attaining this object is a developing unit that can be mounted to and dismounted from an image forming apparatus main unit, the developing unit including:

a memory unit including a memory; and

a label on which information relating to the developing unit is written, and that has been stuck to the developing unit so as to cover the memory unit.

Features and objects of the present invention other than the above will be made clear by reading the present specification with reference to the accompanying drawings.

BRIEF DESCRIPTION OF DRAWINGS

FIG. 1 is a diagram illustrating how developing containers 51, 52, 53 and 54 are mounted to and dismounted from a printer main unit 10a.

FIG. 2 is a diagram showing the main structural components constituting the printer 10.

FIG. 3 is a block diagram showing the control unit 100 of the printer 10.

FIG. 4 is a perspective view of a developing container holding unit 50.

FIG. 5 is a diagram showing the developing container holding unit 50 in a state in which a yellow developing container 54 is mounted to a mounting and dismounting section 50d.

FIG. 6 is a perspective view of the yellow developing container 54.

FIG. 7 is a cross-sectional view showing the main structural components of the yellow developing container 54.

12

FIG. 8 is a perspective view of a developing roller 510 provided with rolls 574.

FIG. 9 is a front view of the coupling member 590.

FIG. 10 is a perspective view showing the rear side of the coupling member 590.

FIG. 11A is a diagram showing the developing container holding unit 50 in a state where the yellow developing container 54 is positioned at the developing position. FIG. 11B is a diagram showing the developing container holding unit 50

10 in a state where the yellow developing container 54 is positioned at the communication position. FIG. 11C is a diagram showing the developing container holding unit 50 in a state where the yellow developing container 54 is positioned at the mounting and dismounting position. FIG. 11D is a diagram

15 showing a state where the developing container holding unit 50 is positioned in its home position.

FIG. 12 is a plan transparent view showing the configuration of the element.

FIG. 13 is a block diagram illustrating the internal configuration of the element and the send/receive section.

FIG. 14 is a diagram illustrating the information stored in a memory cell 54h of the element 54a.

FIG. 15 is an explanatory diagram showing the external configuration of an image forming system.

25 FIG. 16 is a block diagram showing the configuration of the image forming system shown in FIG. 15.

FIG. 17 is a diagram showing an embodiment of an image forming apparatus according to a second invention, and is a transparent front view showing its overall schematic configuration.

30 FIG. 18 is a relational block diagram illustrating its controller.

FIG. 19 is a diagram showing the configuration of its essential parts. FIG. 19(a) is a transparent plan view showing a 35 memory tag (storage element) placed on its developing cartridge side and FIG. 19(b) is a relational block diagram illustrating its communication means.

FIG. 20 is a timing chart illustrating the timing of the image forming operation and the communication operation.

40 FIG. 21 is a diagrammatic plan view showing the state in which its essential parts are unfolded.

FIG. 22 is a transparent front view showing the diagrammatic configuration of a first alternative embodiment of the second invention.

45 FIG. 23 is a transparent front view showing the diagrammatic configuration of a second alternative embodiment of the second invention.

FIG. 24 is a diagram showing an embodiment of an image forming apparatus according to a third invention, and is a 50 transparent front view showing its overall schematic configuration.

FIG. 25 is a relational block diagram illustrating its controller.

FIG. 26 is a diagram showing the configuration of its essential parts. FIG. 26(a) shows a transparent plan view showing a 55 memory tag (storage element) placed on its developing cartridge side and FIG. 26(b) is a relational block diagram illustrating its communication means.

FIG. 27 is a top view illustrating the arrangement of its 60 exhaust duct.

FIG. 28 is a side view illustrating the suction of its exhaust duct.

FIG. 29 is a diagram showing another embodiment, and is a 65 diagrammatic transparent front view showing the configuration of its essential parts.

FIG. 30 is a diagram illustrating the problem. FIG. 30(a) is a diagrammatic transparent front view illustrating the suction

13

with the exhaust duct, and FIG. 30(b) is a diagrammatic transparent front view showing the state during the rotation of its developing cartridge.

FIG. 31 is a diagram showing an embodiment of an image forming apparatus according to a fourth invention, and is a transparent front view showing its overall schematic configuration.

FIG. 32 is a relational block diagram illustrating its controller.

FIG. 33 is a diagram showing the configuration of its essential parts. FIG. 33(a) shows a transparent plan view showing a memory tag (storage element) placed on its developing cartridge side and FIG. 33(b) is a relational block diagram illustrating its communication means.

FIG. 34 is a diagram showing the rotation stop position during stand-by of its developing cartridge. FIG. 34(a) is a diagrammatic transparent view taken from its axial direction and FIG. 34(b) is a diagrammatic transparent view taken from its bottom side.

FIG. 35 is a diagram showing the rotation stop position during operation of its developing cartridge. FIG. 35(a) is a diagrammatic transparent view taken from its axial direction and FIG. 35(b) is a diagrammatic transparent view taken from its bottom side.

FIG. 36 is a graph illustrating the communication characteristics in terms of the separation distance between the antennas of its communication means.

FIG. 37 is a diagram showing another embodiment of the fourth invention, and is a diagrammatic transparent front view showing the configuration of its essential parts.

FIG. 38 is a diagram showing an embodiment of an image forming apparatus according to a fifth invention, and is a transparent front view showing its overall schematic configuration.

FIG. 39 is a relational block diagram illustrating its controller.

FIG. 40 is a diagram showing the configuration of its essential parts. FIG. 40(a) shows a transparent plan view showing a memory tag (storage element) placed on its developing cartridge side and FIG. 40(b) is a relational block diagram illustrating its communication means.

FIG. 41 is a diagrammatic transparent view showing the positional relationship between the memory tag (storage element) on the outer surface of its developing cartridge and other devices.

FIG. 42 is a diagram showing the main structural components constituting a printer 5010.

FIG. 43 is a block diagram showing the control unit of the printer 5010 in FIG. 42.

FIG. 44 is a perspective view of a developing device.

FIG. 45 is a cross-sectional view showing main structural components of this developing device.

FIG. 46 is a perspective view showing an arrangement in which a toner supply roller 5550 is installed in a housing 5540.

FIG. 47 is a perspective view showing an arrangement in which a developing roller 5510 is installed in a holder 5526, which is shown in FIG. 48.

FIG. 48 is a perspective view showing an arrangement in which an upper sealing member 5520 and a regulating blade 5560 are integrated in the holder 5526.

FIG. 49 is a perspective view of a side plate 5580.

FIG. 50 is a perspective view showing an arrangement in which the upper sealing member 5520, the regulating blade 5560 and the developing roller 5510 are integrated in an integrating member 5525.

14

FIG. 51 is a perspective view showing an arrangement in which the integrating member 5525 shown in FIG. 50 is installed in the housing 5540 shown in FIG. 46.

FIG. 52 is a perspective reference view showing the arrangement in FIG. 51 when the side plate 5580 is removed from the integrating member 5525.

FIG. 53 is a perspective view showing an arrangement in which the yellow developing container 5054 is mounted to the holding section 5055d of the YMCK developing unit 5050.

10 FIG. 54 is a plan transparent view showing the configuration of the element 5054a.

FIG. 55 is a block diagram illustrating the internal configuration of the element 5054a.

FIG. 56A is a diagram showing the HP position. FIG. 56B 15 is a diagram showing the communication position of the yellow developing container 5054. FIG. 56C is a diagram showing the mounting and dismounting position of the yellow developing container 5054.

FIG. 57 is a diagrammatic view showing the positional 20 relation between the element 5054a and the main unit-side antenna 5124 when the element 5054a communicates wirelessly with the main unit-side antenna 5124.

BEST MODE FOR CARRYING OUT THE INVENTION

At least the following matters will be made clear by the present specification and the accompanying drawings.

—First Invention—

A main first invention for solving the above-noted object is a developing device that can be mounted to and dismounted from a mounting and dismounting section provided in an image forming apparatus main unit, the developing device including: a developing device main unit; a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in the longitudinal direction of the developing device main unit in such a manner that its relative position to the developing device main unit can be changed; and an element capable of communication in a noncontacting manner with the image forming apparatus main unit side when the developing device is mounted to the mounting and dismounting section, the element being provided at the one end side in the longitudinal direction of the developing device main unit.

With such a developing device, the distance between the element and image forming apparatus main unit side tends not to change, so that it is possible to realize a developing device with which suitable communication with the image forming apparatus main unit side is possible.

In the foregoing developing device, the mounting and dismounting section may be movable; and the developing device may develop a latent image borne on an image bearing member with which the image forming apparatus main unit is provided, when having been moved to a first position through a movement of the mounting and dismounting section while being mounted to the mounting and dismounting section; and the element may communicate in a noncontacting manner with the image forming apparatus main unit side when the developing device has been moved to a second position that is different from the first position.

If the developing device moves with the movement of the mounting and dismounting section, then the relative position of the developing device main unit and the coupling member when the developing device is positioned in the second position changes more easily than in the case that the developing device does not move, so that there is a greater risk that the distance between the image forming apparatus main unit and the element changes. Therefore, if the developing device moves together with the movement of the mounting and dismounting section, the effect that is achieved by providing the element on the one end side, in the longitudinal direction, of the developing device main unit, that is, the effect that it becomes possible to realize a developing device with which suitable communication with the image forming apparatus is possible, can be displayed more effectively.

In the foregoing developing device, the mounting and dismounting section may include a spring that biases the developing device main unit along its longitudinal direction; and the relative position of the developing device main unit and the coupling member may change in accordance with the biasing amount provided by the spring.

If the mounting and dismounting section includes a spring that biases the developing device main unit along its longitudinal direction, then the developing device oscillates due to the extension and contraction of the spring when the developing device is positioned in the second position. And when the developing device oscillates, there is the risk that the distance between the image forming apparatus main unit and the element changes and that the element cannot communicate properly with the image forming apparatus main unit. Therefore, the effect of providing the element on the one end side in the longitudinal direction of the developing device main unit, that is, the effect that a developing device can be realized that can communicate properly with the image forming apparatus main unit can be more effectively displayed in the case that the mounting and dismounting section is provided with a spring.

In the foregoing developing device, the developing device main unit may include: a developer bearing member that bears a developer, and that is for developing the latent image borne on the image bearing member with the developer; and a distance holding member for holding a distance between the image bearing member and the developer bearing member by coming into contact with the image bearing member, the distance holding member being provided on both end portions in a longitudinal direction of the developer bearing member; and the distance holding member may hold the distance by coming into contact with the image bearing member when the developing device has moved to the first position.

In order to suitably develop the latent image carried on the bearing member, it is necessary to hold a suitable distance between the developer holding member and the image bearing member. Then, in order to hold this distance, a distance holding member coming into contact with the image bearing member may be provided at both ends in the longitudinal direction of the developer bearing member. In this case, when the relative position between the coupling member and the developing device main unit provided with the developer bearing member can change, then the distance holding member can come into contact with the image bearing member in order to ensure that the developer bearing member follows the image bearing member even when the image bearing member is attached slanted with respect to the image forming apparatus main unit, so that it is possible to hold a suitable distance between the developer bearing member and the image bearing member.

In the foregoing developing device, the positioning member may be a positioning shaft that is fixed to a side wall on the one end side in a longitudinal direction of the developing device main unit, such that the axial direction of the positioning member coincides with the longitudinal direction of the developing device main unit; and the positioning shaft may position the developing device main unit with respect to the mounting and dismounting section by fitting into a positioning hole provided in the mounting and dismounting section when the developing device has been mounted into the mounting and dismounting section.

If the positioning shaft fits into a positioning hole to position the developing device main unit with respect to the mounting and dismounting section, then the developing device main unit can be positioned with respect to the mounting and dismounting section with a simple configuration.

In the foregoing developing device, the mounting and dismounting section may be provided with a coupling hole; the coupling member may be provided with a coupling protrusion that can be fitted into the coupling hole, the coupling member may be attached to a side wall at the other end side in

the longitudinal direction of the developing device main unit; and the coupling member may be coupled with the mounting and dismounting section by fitting the coupling protrusion in the coupling hole when the developing device has been mounted to the mounting and dismounting section.

If the coupling member is coupled to the mounting and dismounting section by fitting coupling protrusion into the coupling hole, then the coupling member can be coupled with the mounting and dismounting section with a simple configuration.

In the foregoing developing device, the developing device main unit may be provided with an attachment protrusion having a circular cross section; the coupling member may be provided with an attachment hole that has an elliptical cross section and into which the attachment protrusion can be fitted; and the attachment hole may allow movement, within the attachment hole, of the attachment protrusion fitted into the attachment hole.

If the attachment hole allows movement, within the attachment hole, of the attachment protrusion fitted into the attachment hole, then it becomes possible to move the developing device main unit easily with respect to the coupling member with a simple configuration.

In the foregoing developing device, the developing device main unit may be provided with a housing for containing a developer; and the element may be attached to an outer surface of the housing, the outer surface extending along a longitudinal direction of the housing.

In this case, it becomes possible to let the element communicate with the image forming apparatus main unit with a simple configuration.

In the foregoing developing device, the developing device main unit may include a developer bearing member that is supported by the housing at both end portions in its longitudinal direction, and that is for bearing a developer and developing a latent image borne on the image bearing member with the developer; the outer surface of the housing may include a circularly arc-shaped surface whose cross section through a perpendicular plane that is perpendicular to the longitudinal direction of the housing is circularly arc-shaped; and the element may be attached to a position of the circularly arc-shaped surface that is furthest removed from the developer bearing member.

If the element is attached to a position of the circularly arc-shaped surface that is furthest removed from the developer bearing member, then it can be prevented that developer carried by the developer bearing member is scattered and adheres to the element, so that it becomes possible to let the element communicate more properly with the image forming apparatus main unit side.

Furthermore, a developing device that can be mounted to and dismounted from a mounting and dismounting section provided in an image forming apparatus main unit, the developing device, including: a developing device main unit;

a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in the longitudinal direction of the developing device main unit in such a manner that its relative position to the developing device main unit can be changed; and an element capable of

communication in a noncontacting manner with the image forming apparatus main unit side when the developing device is mounted to the mounting and dismounting section, the element being provided at the one end side in the longitudinal direction of the developing device main unit; wherein the mounting and dismounting section is movable; the developing device develops a latent image borne on an image bearing member with which the image forming apparatus main unit is provided, when having been moved to a first position through a movement of the mounting and dismounting section while being mounted to the mounting and dismounting section; the element communicates in a noncontacting manner with the image forming apparatus main unit side when the developing device has been moved to a second position that is different from the first position; the mounting and dismounting section includes a spring that biases the developing device main unit along its longitudinal direction; and the relative position of the developing device main unit and the coupling member changes in accordance with the biasing amount provided by the spring; the developing device main unit includes: a developer-bearing member that bears a developer and that is for developing the latent image borne on the image bearing member with the developer; and a distance holding member for holding a distance between the image bearing member and the developer bearing member by coming into contact with the image bearing member, the distance holding member being provided on both end portions in a longitudinal direction of the developer bearing member; the distance holding member holds the distance by coming into contact with the image bearing member when the developing device has moved to the first position; the positioning member is a positioning shaft that is fixed to a side wall on the one end side in a longitudinal direction of the developing device main unit, such that the axial direction of the positioning member coincides with the longitudinal direction of the developing device main unit; the positioning shaft positions the developing device main unit with respect to the mounting and dismounting section by fitting into a positioning hole provided in the mounting and dismounting section when the developing device has been mounted into the mounting and dismounting section; the mounting and dismounting section is provided with a coupling hole; the coupling member is provided with a coupling protrusion that can be fitted into the coupling hole, and the coupling member being attached to a side wall at the other end side in the longitudinal direction of the developing device main unit; the coupling member is coupled with the mounting and dismounting section by fitting the coupling protrusion in the coupling hole when the developing device has been mounted to the mounting and dismounting section; the developing device main unit is provided with an attachment protrusion having a circular cross section; the coupling member is provided with an attachment hole that has an elliptical cross section and into which the attachment protrusion can be fitted; the attachment hole allows movement, within the attachment hole, of the attachment protrusion fitted into the attachment hole; the developing device main unit is provided with a housing for containing a developer; the element is attached to an outer surface of the housing, the outer surface extending along a longitudinal direction of the housing; the developing device main unit includes a developer bearing member that is supported by the housing at both end portions in its longitudinal direction, and that is for bearing a developer and developing a latent image borne on the image bearing member with the developer; the outer surface of the housing includes a circularly arc-shaped surface whose cross section through a perpendicular plane that is perpendicular to the longitudinal direction of the housing is circularly arc-

shaped; and the element is attached to a position of the circularly arc-shaped surface that is furthest removed from the developer bearing member.

With such a developing device, the effect that it becomes possible to realize a developing device that can communicate suitably with the image forming apparatus main unit side can be displayed most effectively.

Furthermore, an image forming apparatus including: an image bearing member for bearing a latent image; and

10 a developing device that can be mounted to and dismounted from a mounting and dismounting section provided in an image forming apparatus main unit, the developing device including: a developing device main unit; a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in a longitudinal direction of the developing device main unit in such a manner that its relative position to the developing device main unit can be changed; and an element capable of communication in a noncontacting manner with the image forming apparatus main unit side when the developing device is mounted to the mounting and dismounting section, the element being provided at the one end side in the longitudinal direction of the developing device main unit, the developing device being for developing a latent image borne on the image bearing member when being mounted to the mounting and dismounting section.

Such an image forming apparatus is provided with a developing device that can communicate suitably with the image forming apparatus main unit side, so that it becomes possible to realize an image forming apparatus that is superior to the prior art.

Furthermore, an image forming system including: a computer; and an image forming apparatus that can be connected to the computer, the image forming apparatus including: an image bearing member for bearing a latent image; and a developing device that can be mounted to and dismounted from a mounting and dismounting section provided in an image forming apparatus main unit, the developing device including: a developing device main unit; a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in a longitudinal direction of the developing device main unit in such a manner that its relative position to the developing device main unit can be changed; and an element capable of communication in a noncontacting manner with the image forming apparatus main unit side when the developing device is mounted to the mounting and dismounting section, the element being provided at the one end side in the longitudinal direction of the developing device main unit, the developing device being for

developing a latent image borne on the image bearing member when being mounted to the mounting and dismounting section.

Such an image forming system is provided with a developing device that can communicate suitably with the image forming apparatus main unit side, so that it becomes possible to realize an image forming system that is superior to the prior art.

====Second Invention====

A main second invention for solving the above-noted object is an image forming apparatus forming an image by transferring a toner image on a bearing member surface onto a recording medium and fixing that toner image, the image forming apparatus including: a bearing member carrying a toner image obtained by forming an electrostatic latent image on its surface and developing that electrostatic latent image; a developing cartridge for developing the electrostatic latent image by selectively adhering toner to the electrostatic latent image on the surface of the bearing member; a developing rotary unit that accommodates a plurality of the developing cartridges removably around a rotation shaft, and lets one of the developing cartridges oppose the surface of the bearing member by rotating around the rotation shaft; and a controller controlling the driving of various sections of the apparatus, including the bearing member and the developing cartridge, based on received image data and various kinds of information; wherein a storage element storing and holding information relating to the developing cartridge is placed on an outer surface of the developing cartridge, and a communication means is provided that performs communication by reading out at least information inside the storage element as information processed by the controller; the storage element is arranged at a position along the external cover when being stopped near the external cover of the apparatus main unit after being rotated by the developing rotary unit; and that stop position is set as the communication position with the communication means.

In this invention, during communication (in the communication position) in which the rotation is stopped and stored information is exchanged, the storage element on the outer surface of the developing cartridge is positioned at a position along the external cover of the apparatus main unit, or in other words, of the locations where it can be placed on the outer surface of the developing cartridge, at a position that becomes closest to the external cover of the apparatus main unit. Consequently, during communication, the storage element on the outer surface of the developing cartridge can perform the reading or writing of storage information in an environment that is close to the external temperature, via the external cover of the apparatus main unit, and the thermal influence from devices that are heat-generating members within the device main unit can be reduced.

A second second invention of a developing device solving the above-noted object is one, wherein, in addition to the features of the main second invention, the storage element in the communication position is positioned in a region in which it is furthest removed from a heat-generating member within the apparatus main unit.

With this invention, during communication, the storage element on the outer surface of the developing cartridge is closest to the external cover of the apparatus main unit, and at the same time its communication position is set such that it is positioned at a region that is furthest removed from heat-generating members within the apparatus main unit. Consequently, the storage element on the outer surface of the developing cartridge is in an environment that is close to the

external temperature, via the external cover of the apparatus main unit, and the thermal influence from devices that are heat-generating members within the apparatus main unit can be reduced to a minimum.

5 A third second invention of a developing device solving the above-noted object is one, wherein, in addition to the features of the main second invention or the second second invention, the external cover is provided with a vent hole near the storage element positioned in the communication position.

10 With this invention, during communication, the storage element on the outer surface of the developing cartridge is closest to the external cover of the apparatus main unit, and is exposed to external air flowing in from the vent hole in the external cover. Consequently, the storage element on the outer surface of the developing cartridge is in an environment that is close to the external temperature outside the apparatus main unit, and the reading or writing of storage information can be carried out while effectively avoiding the occurrence of errors or a decrease in processing performance.

15 20 A fourth second invention of an image forming apparatus solving the above-noted object is one, which, in addition to the features of any of the main second invention to the third second invention, further includes a ventilation means that blows air onto a member surface near the storage element by forcibly generating an air-flow near the storage element in the communication position.

25 30 With this invention, during communication, the storage element on the outer surface of the developing cartridge is closest to the external cover of the apparatus main unit, and is exposed to a forcibly generated stream of air. Consequently, by forcibly blowing air that is close to the external temperature outside the apparatus main unit onto the storage element on the outer surface of the developing cartridge, heat is carried away, and it can be avoided that the temperature rises, and the reading or writing of stored information can be carried out while effectively avoiding the occurrence of errors or a decrease in processing performance.

35 40 A fifth second invention of an image forming apparatus solving the above-noted object is one, which, in addition to the features of the fourth second invention, further includes an exhaust duct that sucks in a portion inside the apparatus main unit and exhausting it out of the apparatus; wherein the exhaust duct is provided with a drainage opening near the storage element in the communication position and the ventilation means forcibly generates the air-flow near the storage element by sucking in surrounding air into the exhaust duct.

45 50 55 With this invention, during communication, the storage element on the outer surface of the developing cartridge is at a position closest to the external cover of the apparatus main unit, and is exposed to a stream of air that is generated by sucking in surrounding air from a suction opening in the exhaust duct. Consequently, it can be avoided, without providing a separate ventilation device, that the temperature of the storage element on the outer surface of the developing cartridge rises, and the reading or writing of stored information can be carried out while effectively avoiding the occurrence of errors or a decrease in processing performance.

60 65 A sixth second invention of an image forming apparatus solving the above-noted object is one, which, in addition to the features of any of the main second invention to the fifth second invention, antennas are provided at positions where the developing cartridge side can face the apparatus main unit side, providing the communication means with a function of performing communication in a noncontacting manner, and the antenna on the developing cartridge side is adjacent to the storage element.

31

With this invention, the storage element on the outer surface of the developing cartridge is adjacent to an antenna of the communication means, and furthermore, during communication, faces the antenna on the apparatus main unit side. Consequently, in addition to the storage element on the outer surface of the developing cartridge, also both antennas on the developing cartridge side and on the apparatus main unit side as well as the structural components on the apparatus main unit side controlling the communication via this antenna are in an environment that is close to the external temperature, so that communication in a noncontacting manner processing as well as the reading or writing of stored information can be carried out while effectively avoiding the occurrence of errors or a decrease in processing performance.

Furthermore, it may be an image forming apparatus including: a bearing member for bearing an electrostatic latent image; a developing cartridge for developing the electrostatic latent image by selectively adhering a toner to the electrostatic latent image on a surface of the bearing member; a developing rotary unit that is provided in an apparatus main unit, that accommodates a plurality of the developing cartridges that can be inserted and removed around a rotation shaft, and lets one of the developing cartridges oppose the surface of the bearing member by rotating around the rotation shaft; and a storage element that stores and holds information relating to the developing cartridge, the storage element being provided at a position on an outer surface of the developing cartridge where its distance to an external cover of the apparatus main unit is shortest when the memory element communicates with the apparatus main unit after having been stopped in that stop position of the plurality of stop positions, at which the developing cartridge stops when being rotatively moved by the developing rotary unit, in which the outer surface of the developing cartridge is closest to the external cover.

With such an image forming apparatus, the position at which the developing cartridge stops when the storage element and the apparatus main unit communicate, is the stop position, of the plurality of stop positions, at which the outer surface of the developing cartridge and the external cover are closest, and the position on the outer surface at which the storage element is provided is the stop position where distance between the storage element and the external cover becomes smallest, so that during communication, storage information can be read and written at a temperature on the outside of the external cover, that is, in an environment close to the external temperature. Therefore, the thermal influence from portions that are heat-generating members within the apparatus main unit is low, and favorable communication can be performed.

In the foregoing image forming apparatus, it is preferable that in the position in which the apparatus main unit communicates with the storage element, the storage element is positioned in a region in which it is furthest removed from a heat-generating member within the apparatus main unit.

With this image forming apparatus, during communication, the storage element on the outer surface of the developing cartridge is closest to the external cover of the apparatus main unit, and at the same time its communication position is set such that it is positioned at a region that is furthest removed from heat-generating members within the apparatus main unit. Therefore, at the position where the apparatus main unit and the storage element communicate, it is arranged at a position that is furthest removed from the heat-generating members and whose temperature within the apparatus is low, while being closest to the external cover next to the outside air of a temperature that is lower than the temperature within the

32

apparatus, which has risen due to the heat-generating members, so that the temperature of the storage element can be kept from rising, and by suppressing the influence of a temperature rise on communication, favorable communication with the apparatus main unit can be ensured.

In the foregoing image forming apparatus, it is preferable that the external cover is provided with a vent hole near the position in which the apparatus main unit communicates with the storage element.

With this image forming apparatus, the storage element on the outer surface of the developing cartridge is closest to the external cover of the apparatus main unit in the position in which the apparatus main unit communicates with the storage element. Therefore, by forming a vent hole in the external cover, the storage element is exposed to outside air entering through the vent hole, cooling the storage element. Consequently, the storage element on the outer surface of the developing cartridge is in an environment that is close to the external temperature outside the apparatus main unit, and the reading or writing of stored information can be carried out while effectively avoiding the occurrence of errors or a decrease in processing performance.

In the foregoing image forming apparatus, it is preferable that there is provided in the position in which the apparatus main unit communicates with the storage element, a ventilation means that blows air onto a member surface near the storage element by forcibly generating an air-flow near the storage element.

With this image forming apparatus, air is blown onto a member surface near the storage element due to an air-flow generated forcibly by the ventilation means. That is to say, in the position in which the apparatus main unit communicates with the storage element, the storage element on the outer surface of the developer cartridge is forcibly exposed to air that is blown by the ventilation means. Consequently, by forcibly blowing air onto the storage element on the outer surface of the developing cartridge, heat is carried away, and it can be avoided that the temperature rises, and the reading or writing of storage information can be carried out while effectively avoiding the occurrence of errors or a decrease in processing performance.

In the foregoing image forming apparatus, it is preferable that there is provided an exhaust duct, which is provided with a drainage opening near the storage element at the position in which the apparatus main unit communicates with the storage element and that is for sucking air inside the apparatus main unit and exhausting it out of the apparatus; wherein the ventilation means forcibly generates the air-flow near the storage element by sucking air into the exhaust duct.

With such an image forming apparatus, the drainage opening of the exhaust duct is formed near the storage element at the position in which the apparatus main unit communicates with the storage element, so that an air-flow around the storage element is generated by sucking in air from the drainage opening of the exhaust duct. Consequently, due to the generated air-flow, it can be avoided, without providing a separate ventilation device, that the temperature of the storage element on the outer surface of the developing cartridge rises, and the reading or writing of stored information can be carried out while effectively avoiding the occurrence of errors or a decrease in processing performance.

In the foregoing image forming apparatus, it is preferable that antennas are provided at positions where the developing cartridge side faces the apparatus main unit side, allowing the storage element and the apparatus main unit to communicate in a noncontacting manner, and the antenna on the developing cartridge side is adjacent to the storage element.

With this image forming apparatus, the antennas of the apparatus main unit side and of the developing cartridge side oppose each other contactlessly and perform communication in a noncontacting manner. Therefore, it is possible to quickly access the storage element on the outer surface of the developing cartridge without performing a control operation, as for example in the case when a contact on the apparatus main unit side physically contacts a contact on the storage element side, such as moving one of the contacts in order to establish contact between the contacts. Moreover, the antenna is adjacent to the storage element, so that the antenna is arranged in substantially the same environment as the storage element, and the communication process in a noncontacting manner as well as the reading or writing of stored information can be carried out while effectively avoiding the occurrence of errors or a decrease in processing performance. For example, if the antenna is closest to the external cover, like the storage element, then the reading or writing of storage information can be carried out favorably in an environment that is close to the external temperature, and if the storage element is positioned in a region that is furthest removed from the heat-generating members, then also the antenna is furthest removed from the heat-generating members, so that favorable communication can be performed with little thermal influence.

—Third Invention—

A main third invention of an image forming apparatus solving the above-noted object is an image forming apparatus forming an image by transferring a toner image on a bearing member surface onto a recording medium and fixing the toner image, the image forming apparatus including: a bearing member carrying a toner image made by forming an electrostatic latent image based on image data on a surface and developing that electrostatic latent image; a developing cartridge developing the electrostatic latent image by selectively adhering toner to the electrostatic latent image on the bearing member surface; a developing rotary unit accommodating a plurality of the developing cartridges removably around a rotation shaft and letting one of the developing cartridges face the bearing member surface by rotating around the rotation shaft; and a controller controlling the driving of various sections of the apparatus, including the bearing member and the developing cartridge, based on received image data and various kinds of information; the image forming apparatus being further provided with a duct sucking in toner that drifts in a vicinity of a developing position at which the developing cartridge adheres toner to the electrostatic latent image on the surface of the developing member, by providing suction near the developing position; a storage element storing and holding information relating to the developing cartridge placed on an outer surface of the developing cartridge, and a communication means that performs communication by reading out at least information inside the storage element as information processed by the controller, wherein the storage element is arranged outside a region of the outer surface of the developing cartridge that passes near the suction opening of the duct.

With this invention, even when toner drifts near the suction opening of the duct, the storage element on the outer surface of the developing cartridge is not moved near it, and the drifting toner will not come into contact with the storage element and pollute it. Consequently, the storage element on the outer surface of the developing cartridge is not adversely influenced by substances adhering to it, and even when a connection section that is connected communicably with the apparatus main unit side is placed adjacent to this storage element, connection faults will not occur, and the information stored in the storage element can be reliably exchanged.

A second third invention of an image forming apparatus solving the above-noted object is one, wherein, in addition to the features of the main third invention, the communication means has a function of performing communication in a noncontacting manner, with antennas being placed at positions where the developing cartridge side can face the apparatus main unit side, and the antenna on the developing cartridge side is adjacent to the storage element.

With this invention, the antennas of the apparatus main unit side and the developing cartridge side face each other contactlessly and perform communication in a noncontacting manner, so that it is possible to quickly access the storage element on the outer surface of the developing cartridge without performing a control operation such as moving in order to establish contact, and even when the antenna is adjacent to the storage element, toner drifting near the suction opening of the duct will not accumulate on the surface of that antenna. Consequently, communication faults (connection faults) do not occur during the communication in a noncontacting manner, and the information stored in the storage element can be reliably exchanged.

A third second invention of an image forming apparatus solving the above-noted object is an image forming apparatus forming an image by transferring a toner image on a bearing member surface onto a recording medium and fixing the toner image, the image forming apparatus including: a bearing member carrying a toner image made by forming an electrostatic latent image based on image data on a surface and developing that electrostatic latent image; a developing cartridge developing the electrostatic latent image by selectively adhering toner to the electrostatic latent image on the bearing member surface; a developing rotary unit accommodating a plurality of the developing cartridges removably around a rotation shaft and letting one of the developing cartridges face the bearing member surface by rotating around the rotation shaft; and a controller controlling the driving of various sections of the apparatus, including the bearing member and the developing cartridge, based on received image data and various kinds of information; the image forming apparatus being further provided with a duct sucking in toner that drifts in a vicinity of a developing position at which the developing cartridge adheres toner to the electrostatic latent image on the surface of the developing member, by providing suction near the developing position; a storage element storing and holding information relating to the developing cartridge placed on an outer surface of the developing cartridge, and a communication means that performs communication by reading out at least information inside the storage element as information processed by the controller; wherein a position outside the region on the outer surface of the developing cartridge that passes a vicinity of the suction opening of the duct is set as a communication position for communication with the communication means, which is connected such that it can exchange storage information with the storage means.

With this invention, even when toner drifts near the suction opening of the duct, the connection section for providing a connection to the storage element on the outer surface of the developing cartridge is not moved near it, and the drifting toner will not come into contact with this connection element and pollute it. Consequently, the connection element on the outer surface of the developing cartridge can be connected such that it can communicate with the apparatus main unit side, without the occurrence of connection faults, and the information stored in the storage element can be reliably exchanged.

A fourth third invention of an image forming apparatus solving the above-noted object is one, wherein, in addition to

35

the features of the third invention, the communication means has a function of performing communication in a noncontacting manner, with antennas being placed at positions where the developing cartridge side faces the apparatus main unit side, and the antenna facing position is set to the communication position.

With this invention, the antennas (communication sections) on the apparatus main unit side and the developing cartridge side face each other contactlessly and perform communication in a noncontacting manner, so that it is possible to quickly access the storage element on the outer surface of the developing cartridge without performing a control operation such as moving in order to establish contact, and toner drifting near the vicinity of the suction opening of the duct does not accumulate on the antenna surfaces. Consequently, communication faults (connection faults) do not occur during the communication in a noncontacting manner, and the information stored in the storage element can be reliably exchanged.

Furthermore, it is an image forming apparatus including: a bearing member for bearing an electrostatic latent image; a developing cartridge for developing the electrostatic latent image by selectively adhering a toner to the electrostatic latent image on a surface of the bearing member; a developing rotary unit provided in an apparatus main unit, that accommodates a plurality of the developing cartridges that can be inserted and removed around a rotation shaft, and lets one of the developing cartridges oppose the surface of the bearing member by rotating around the rotation shaft; a duct having a suction opening for sucking a toner that drifts in a vicinity of a developing position at which the developing cartridge adheres a toner to the electrostatic latent image on the surface of the developing member, by providing suction near the developing position; and a storage element capable of communication with the apparatus main unit, that stores and holds information relating to the developing cartridge, the storage element being provided on an outer surface of the developing cartridge to the outside of a region facing a part of the duct where the suction opening is formed, when the developing cartridge is rotated and passes the vicinity of the suction opening.

With such an image forming apparatus, when the developing cartridge is rotated and passes the vicinity of the suction opening, the storage element does not pass the vicinity of the suction opening. Therefore, even when the toner drifts in the vicinity of the suction opening of the duct, it is possible to keep the drifting toner from adhering to the storage element. Consequently, the storage element on the outer surface of the developing cartridge is not adversely affected by substances adhering to it, so that it is possible to accomplish favorable communication between the storage element and the apparatus main unit, and to reliably exchange the information inside the storage element.

In the foregoing image forming apparatus, it is preferable that the storage element and the apparatus main unit include communication sections for communicating; wherein antennas are placed at positions where the developing cartridge side faces the apparatus main unit side, so that the communication sections have a function of performing communication in a noncontacting manner, and the antenna on the developing cartridge side is adjacent to the storage element.

With such an image forming apparatus, the antennas on the apparatus main unit side and on the developing cartridge side face each other without contacting each other and perform communication in a noncontacting manner. Therefore, it is possible to quickly access the storage element on the outer surface of the developing cartridge without performing a control operation, as for example in the case when a contact

36

on the apparatus main unit side physically contacts a contact on the storage element side, such as moving one of the contacts in order to establish contact between the contacts. Moreover, the antenna is adjacent to the storage element, so that there is little possibility that the antenna passes near the suction opening of the duct when the developing cartridge is moved. Therefore, toner drifting in the vicinity of the suction opening of the duct does not tend to accumulate on the antenna surface. Consequently, communication faults (connection faults) do not occur during the communication in a noncontacting manner, and the information stored in the storage element can be reliably exchanged.

Furthermore, it may be an image forming apparatus including: a bearing member for bearing an electrostatic latent image; a developing cartridge for developing the electrostatic latent image by selectively adhering toner to the electrostatic latent image on a surface of the bearing member; a developing rotary unit provided in an apparatus main unit, that accommodates a plurality of the developing cartridges that can be inserted and removed around a rotation shaft, and lets one of the developing cartridges oppose the surface of the bearing member by rotating around the rotation shaft; a duct having a suction opening for sucking a toner that drifts in a vicinity of a developing position at which the developing cartridge adheres a toner to the electrostatic latent image on the surface of the developing member, by providing suction near the developing position; a storage element for storing and holding information relating to the developing cartridge; and communication sections for letting the apparatus main unit and the storage element communicate with each other, the communication sections being placed to the outside, in a direction along the rotation shaft, of a part of the duct where the suction opening is formed.

With such an image forming apparatus, the communication sections for establishing communication between the storage element and the apparatus main unit are arranged to the outside, in a direction parallel to the rotation shaft, of a position of the duct where the suction opening is formed. Therefore, even when the toner drifts near the suction opening of the duct, this drifting toner can be kept from adhering to the communication sections during the communication between the storage element and the apparatus main unit. Consequently, the communication section on the outer surface of the developing cartridge is not adversely affected by substances adhering to it, so that it is possible to accomplish favorable communication between the storage element and the apparatus main unit, and to reliably exchange the information inside the storage element.

In this image forming apparatus, it is preferable that the communication sections include a developing cartridge-side antenna and an apparatus main unit-side antenna for letting the storage element and the apparatus main unit communicate with each other, the developing cartridge-side antenna and the apparatus main unit-side antenna facing each other outside, in a direction along the rotation shaft, of a part of the duct where the suction opening is formed, so that the storage element and the apparatus main unit perform communication in a noncontacting manner.

With such an image forming apparatus, the antennas on the apparatus main unit side and on the developing cartridge side face each other without contacting each other and perform communication in a noncontacting manner. Therefore, it is possible to quickly access the storage element provided on the developing cartridge side without performing a control operation, as for example in the case when a contact on the apparatus main unit side physically contacts a contact on the storage element side, such as moving one of the contacts in

order to establish contact between the contacts. Moreover, the storage element and the apparatus main unit communicate with each other with the developing cartridge-side antenna and the apparatus main unit-side antenna facing each other outside, in a direction parallel to the rotation shaft, of a position of the duct where the suction opening is formed, so that communication faults (connection faults) due to the influence of toner drifting around the duct do not occur during the communication in a noncontacting manner, and the information stored in the storage element can be reliably exchanged.

====Fourth Invention====

A main fourth invention of an image forming apparatus solving the above-noted object is an image forming apparatus that forms an image by transferring a toner image on a bearing member surface onto a recording medium and fixing the toner image, the image forming apparatus including: a bearing member that bears a toner image made by forming an electrostatic latent image based on image data on a surface and developing that electrostatic latent image; an exposing unit that forms the electrostatic latent image based on the image data by selectively scanning and exposing the bearing member surface; a developing cartridge that develops the electrostatic latent image by selectively adhering toner to the electrostatic latent image on the bearing member surface; a developing rotary unit that accommodates a plurality of the developing cartridges that can be inserted and removed around a rotation shaft and lets one of the developing cartridges face the bearing member surface by rotating around the rotation shaft; and a controller that controls the driving of various sections of the apparatus, including the bearing member and the developing cartridge, based on received image data and various kinds of information; wherein a storage element storing and holding information relating to the developing cartridge is placed on an outer surface of the developing cartridge, and a communication means is provided that performs communication by reading out at least information inside the storage element as information to be processed by the controller; and wherein the storage element is arranged outside a position facing a heat-generating member when the rotation of the developing cartridge is stopped.

With this invention, the storage element on the outer surface of the developing cartridge whose rotation has been stopped comes to rest outside a position facing heat-generating members serving as heat sources inside the apparatus main unit. Consequently, the temperature of storage element on the surface of the developing cartridge does not rise due to receiving the heat generated by the heat-generating members giving off heat inside the apparatus main unit while rotation is stopped, and it is possible to read and write the storage information inside the storage element at a temperature at which ordinary operation is possible, when the operation is resumed.

A second fourth invention of an image forming apparatus solving the above-noted object is one, wherein, in addition to the features of the main fourth invention, the heat-generating member is a scanner motor that rotates, at high speed, within the exposing unit in order to scan laser light that exposes the bearing member surface, or a driver section that controls the driving of the scanner motor.

With this invention, even when the scanner motor of the exposing motor or the driver section give off heat during driving, they do not face the storage element on the outer surface of the developing cartridge. Consequently, even when for example the scanner motor rotates at higher speeds and becomes hotter, as the image forming apparatus becomes faster, or the layout is such that the outer surface of the

developing cartridge comes close to the exposing unit, as the apparatus becomes smaller, the storage element on the outer surface of the developing cartridge is not unnecessarily heated, so that it is possible to strive for higher speeds and smaller sizes without being restricted by the heating of the storage element.

A third fourth invention of an image forming apparatus solving the above-noted object is one, wherein, in addition to the features of the main fourth invention or the second fourth invention, the communication section has a function of performing communication in a noncontacting manner, with antennas being placed at positions where the developing cartridge side faces the apparatus main unit side, and the antenna on the developing cartridge side is adjacent to the storage element.

In this invention, not only the storage element on the outer surface of the developing cartridge, but also structural components performing communication control by facing contactlessly the antenna of the apparatus main unit side during communication come to rest outside a position opposing heat-generating members such as the exposing unit, which is a heat source inside the apparatus main unit, when rotation is stopped. Consequently, there is no drop in the processing capability of the communication in a noncontacting manner due to the amount of heat received from the heat-generating members giving off heat within the apparatus main unit while the rotation of the developing cartridge is stopped, and it is possible to exchange the storage information within the storage element at a temperature at which proper operation is possible, and to perform reading and writing.

A fourth fourth invention of an image forming apparatus solving the above-noted object is one, wherein, in addition to the features of any of the main fourth invention to the third fourth invention, the storage element is arranged at a position that is removed, in the rotation direction, from a position where the heat-generating member faces an outer surface of the developing cartridge whose rotation is stopped.

With this invention, when the rotation of the developing cartridge is stopped, the storage element on the outer surface of the developing device comes to rest at a position that is offset with respect to the rotation direction from a position facing the heat-generating member serving as a heat source inside the apparatus main unit. Consequently, even when the storage element is placed on the outer surface of the developing cartridge facing a heat-generating member inside the apparatus main unit during rotation, it is at least avoided that it stops in a condition where they face, its temperature does not rise due to receiving the amount of heat from the heat-generating member that is radiated inside the apparatus main unit when the rotation is stopped directly next to the heat source, and it is possible to read and write the storage information inside the storage element at a temperature at which ordinary operation is possible, when the operation is resumed.

A fifth fourth invention of an image forming apparatus solving the above-noted object is one, wherein, in addition to the features of the fourth fourth invention, the developing cartridge includes a developing roller that adheres contained toner onto the bearing member surface; and also the developing roller is arranged at a position that is removed, in the rotation direction, from a position where the heat-generating member faces an outer surface of the developing cartridge whose rotation is stopped.

With this invention, the developing roller of the developing cartridge, like the storage element on its outer surface, comes to rest at a position that is removed, in the rotation direction, from a position facing the heat-generating member, which is

a heat source, inside the apparatus main unit, when the rotation of this developing cartridge is stopped. Consequently, as in the case of the storage element, it is avoided that it stops in a condition where it faces a heat-generating member inside the apparatus main unit, it is avoided that it is affected by the amount of heat from the heat-generating member that is radiated inside the apparatus main unit when the rotation is stopped in a state in which it is directly next to the developing roller itself or the toner on its circumferential surface, and it is possible to develop the electrostatic latent image on the bearing member surface with high quality, when the operation is resumed.

A sixth fourth invention of an image forming apparatus solving the above-noted object is one, wherein, in addition to the features of any of the main fourth invention to the fifth fourth invention, the storage element is arranged at a position that is removed, in an axial direction of the rotation shaft, from a position where the heat-generating member faces an outer surface of the developing cartridge whose rotation is stopped.

With this invention, the storage element on the outer surface of the developing cartridge comes to rest at a position that is removed, in the axial direction of the rotation shaft, from a position facing a heat-generating member that is a heat source inside the apparatus main unit. Consequently, the storage element on the outer surface of the developing cartridge does not oppose the heat-generating member inside the apparatus main unit, it is possible to avoid more reliably that its temperature rises due to receiving the amount of heat from the heat-generating member giving off heat inside the apparatus main unit, and it is possible to read and write the storage information within the storage element at a temperature at which proper operation is possible, after the operation is resumed.

==Fifth Invention==

A main fifth invention of an image forming apparatus solving the above-noted object is an image forming apparatus that forms an image by transferring a toner image on a bearing member surface onto a recording medium and fixing the toner image, the image forming apparatus including: a bearing member that bears a toner image made by forming an electrostatic latent image based on image data on a surface and developing that electrostatic latent image; a developing cartridge that develops the electrostatic latent image by selectively adhering toner to the electrostatic latent image on the bearing member surface; a developing rotary unit that accommodates a plurality of the developing cartridges that can be inserted or removed around a rotation shaft and lets one of the developing cartridges face the bearing member surface by rotating around the rotation shaft; a controller that controls the driving of various sections of the apparatus, including the bearing member and the developing cartridge, based on received image data and various kinds of information; the image forming apparatus further including: a storage element that stores and holds information relating to the developing cartridge, placed on an outer surface of the developing cartridge, and a communication means that has a function of performing communication in a noncontacting manner, with antennas being placed at positions where the developing cartridge side can face the apparatus main unit side, and that performs communication in a noncontacting manner by reading out at least information inside the storage element as information processed by the controller; wherein a blocking member is placed between a high-voltage member, which takes on a voltage equal or greater than that which is necessary for the adherence and transfer of a toner, and a rotation

trajectory of the storage element on the outer surface of the developing cartridge, the blocking member limiting the influence that noise caused by the high-voltage member has on the storage element.

5 With this invention, even when noise emanates toward the storage element from the high-voltage member that is provided because electrophotography is employed, then the adverse influence that this noise may have is restricted, for example by being absorbed by the blocking member before it reaches the storage element. Consequently, it is avoided that the storage information inside the storage element is rewritten (corrupted) or deleted.

A second fifth invention of an image forming apparatus solving the above-noted object is one, wherein, in addition to the features of the main fifth invention, the storage element is placed on the outer surface of the developing cartridge, adjacent to the developing cartridge-side antenna.

With this invention, it is avoided that the noise from the high-voltage element is picked up by the antenna and 20 adversely influences the storage information of the storage element. Consequently, even with a layout in which the antenna is close to the storage element and noise from the high-voltage element is easily picked up, it is avoided that the storage information inside the storage element is rewritten (corrupted) or deleted.

A third fifth invention of an image forming apparatus solving the above-noted object is one, wherein, in addition to the features of the main fifth invention or the second fifth fourth invention, the high-voltage member includes either one or 30 both of a voltage applying member, which charges a contacting member with a high voltage, or that charged member.

With this invention, since the member for transferring the toner is charged, and since the voltage applying member applies a high charging voltage to the charged member, if 35 noise is given off to the surroundings, then the adverse influence that this noise may have is restricted, for example by being absorbed by the blocking member before it reaches the storage element. Consequently, it is possible to lay out the voltage applying member and the charged member inside the 40 apparatus without restrictions due to the placement of the storage element on the outer surface of the developing cartridge.

A fourth fifth invention of an image forming apparatus solving the above-noted object is one, wherein, in addition to the features of the third fifth invention, the charged member is a bearing member bearing a toner image obtained by developing the electrostatic latent image, and the voltage applying member is a member charging the bearing member surface to a potential at which the electrostatic latent image is formed and toner is adhered.

With this invention, the noise stemming from the bearing member bearing the toner image that is developed by forming an electrostatic latent image, or the member charging this bearing member, such that this electrostatic latent image can 55 be formed or the toner image can be carried, is absorbed by the blocking member, so that the adverse influence it has on the storage element is restricted. Consequently, it is avoided that the storage information inside the storage element is rewritten (corrupted) or deleted, in the surroundings of the bearing member.

A fifth fifth invention of an image forming apparatus solving the above-noted object is one, which, in addition to the features of the third fifth invention or the fourth fifth invention, is provided with an intermediate image transfer member that, after a toner image on the bearing member surface has been transferred to it by primary image transfer, performs secondary image transfer of the toner image onto a recording

41

medium; wherein the charged member is the intermediate image transfer member, and the voltage applying member is a member that charges the intermediate image transfer member to a potential at which the toner image is borne after receiving it from the bearing member.

With this invention, the noise from the intermediate image transfer member receiving the toner image carried by the bearing member and transferring it to the recording medium and from the member charging this intermediate image transfer member such that the carrying of this toner image is possible is absorbed by the blocking member, so that the adverse influence it has on the storage element is restricted. Consequently, it is avoided that the storage information inside the storage element is rewritten (corrupted) or deleted, in the surroundings of the intermediate image transfer member.

A sixth fifth invention of an image forming apparatus solving the above-noted object is one, wherein, in addition to the features of any of the main fifth invention to the fifth fifth invention, the blocking member is placed at a position where the high-voltage member faces the antenna or the storage element.

With this invention, the blocking member is placed at a location with an orientation at which the high-voltage member substantially faces the antenna or the storage element, and the noise from this high-voltage member is absorbed and its adverse influence is restricted. Consequently, at a timing in which the storage element is rotated to a location where it is easily affected by noise, it is prevented that this noise is picked up and it is effectively avoided that the storage information inside the storage element is rewritten (corrupted) or deleted.

====Sixth Invention=====

A developing device that can be mounted to and dismounted from an image forming apparatus main unit, the developing device including: an element that, when the developing device is mounted to the image forming apparatus main unit, faces, across a gap, an antenna provided to the image forming apparatus main unit, and is capable of wireless communication with the antenna; and a metal plate, at least a portion of which is positioned to the outer side of the gap and at a position corresponding to the gap in a direction from the element toward the antenna, when the developing device is mounted to the image forming apparatus main unit and the element performs wireless communication with the antenna.

In this case, a developing device is realized, with which the amount of noise intruding into the gap between the element and the antenna is suitably reduced when wireless communication is performed between the element and the antenna.

The developing device may include: a developer bearing roller provided extending along a longitudinal direction of the developing device, that is for bearing a developer; a first driving wheel provided at one end portion of the developer bearing roller, that is for driving the developer bearing roller; and a second driving wheel that receives a driving force from the image forming apparatus main unit when the developing device is mounted to the image forming apparatus main unit, and that transmits the driving force to the first driving wheel; and the metal plate may be a positioning member for positioning the first driving wheel and the second driving wheel.

In this case, it is more efficient with regard to the fact that one member has a plurality of functions.

The element may be provided at an end portion, in the longitudinal direction of the developing device, at which the first driving wheel is positioned.

42

In this case, the element is positioned at a position that is closer to the metal plate, so that the metal plate can more suitably reduce the amount of noise that intrudes into the gap.

It is also possible to realize an image forming apparatus including: an image forming apparatus main unit including an antenna; and a developing device that can be mounted to and dismounted from the image forming apparatus main unit, the developing device including: an element that, when the developing device is mounted to the image forming apparatus main unit, faces the antenna across a gap, and is capable of wireless communication with the antenna; and a metal plate, at least a portion of which is positioned to the outer side of the gap and at a position corresponding to the gap in a direction from the element toward the antenna, when the developing device is mounted to the image forming apparatus main unit and the element performs wireless communication with the antenna.

In this case, an image forming apparatus is realized, with which the amount of noise intruding into the gap between the element and the antenna is suitably reduced when wireless communication is performed between the element and the antenna.

Furthermore, the image forming apparatus main unit may include a rotatable rotating member including a mounting and dismounting section to which the developing device can be mounted and dismounted; and the element may perform wireless communication with the antenna, when the developing device has been rotated through rotation of the rotating member with the developing device mounted in the mounting and dismounting section, so that the element provided on the developing device faces the antenna across the gap.

Furthermore, the developing device may include: a developer bearing roller for bearing a developer, that is provided extending along a longitudinal direction of the developing device; a first driving wheel for driving the developer bearing roller, that is provided at a one end portion of the developer bearing roller; and a second driving wheel that receives a driving force from the image forming apparatus main unit when the developing device is mounted to the image forming apparatus main unit, and that is for transmitting the driving force to the first driving wheel; wherein the metal plate is a positioning member for positioning the first driving wheel and the second driving wheel. In this case, it is more efficient with regard to the fact that one member has a plurality of functions.

Furthermore, the element may be provided at an end portion, in a longitudinal direction of the developing device, at which the first driving wheel is positioned.

In this case, the element is positioned at a position that is closer to the metal plate, so that the metal plate can more suitably reduce the amount of noise that intrudes into the gap.

Furthermore, the image forming apparatus main unit may include a motor; and the metal plate may be positioned between the motor and the gap when the element communicates wirelessly with the antenna.

In this case, the above-noted effect, that is, the effect that the amount of noise intruding into the gap is reduced, is displayed more effectively.

Furthermore, the image forming apparatus main unit may include a main unit-side metal plate at least a portion of which is positioned to an outer side of the gap and at a position corresponding to the gap in a direction from the element toward the antenna, when the element communicates wirelessly with the antenna.

In this case, it becomes possible to more suitably reduce the amount of noise intruding the gap between the element and the antenna when the element communicates wirelessly with the antenna.

Furthermore, it is possible to realize an image forming apparatus including: an image forming apparatus main unit including an antenna; and a developing device that can be mounted to and dismounted from the image forming apparatus main unit, the developing device including: an element that, when the developing device is mounted to the image forming apparatus main unit, faces the antenna across a gap, and is capable of wireless communication with the antenna; and a metal plate, at least a portion of which is positioned to the outer side of the gap and at a position corresponding to the gap in a direction from the element toward the antenna, when the developing device is mounted to the image forming apparatus main unit and the element performs wireless communication with the antenna; wherein the image forming apparatus main unit includes a rotatable rotating member including a mounting and dismounting section to which the developing device can be mounted and dismounted; the element performs wireless communication with the antenna, when the developing device has been rotated through rotation of the rotating member with the developing device mounted in the mounting and dismounting section, so that the element provided on the developing device faces the antenna across the gap; the developing device includes: a developer bearing roller for bearing a developer, that is provided extending along a longitudinal direction of the developing device; a first driving wheel for driving the developer bearing roller that is provided at one end of the developer bearing roller; and a second driving wheel that receives a driving force from the image forming apparatus main unit when the developing device is mounted to the image forming apparatus main unit, and that is for transmitting the driving force to the first driving wheel; wherein the metal plate is a positioning member for positioning the first driving wheel and the second driving wheel; the element is provided at an end portion, in a longitudinal direction of the developing device, at which the first driving wheel is positioned; the image forming apparatus main unit includes a motor; the metal plate is positioned between the motor and the gap when the element communicates wirelessly with the antenna; and the image forming apparatus main unit includes a main unit-side metal plate at least a portion of which is positioned to an outer side of the gap and at a position corresponding to the gap in a direction from the element toward the antenna, when the element communicates wirelessly with the antenna.

Thus, the object of the present invention is attained more effectively, since all of the above-noted effects are attained.

Furthermore, it is possible to realize an image forming system including: a computer; and an image forming apparatus that can be connected to the computer the image forming apparatus including: an image forming apparatus main unit including an antenna; and a developing device that can be mounted to and dismounted from the image forming apparatus main unit, the developing device including: an element that, when the developing device is mounted to the image forming apparatus main unit, faces the antenna across the gap, and is capable of wireless communication with the antenna; and a metal plate, at least a portion of which is positioned to the outer side of the gap and at a position corresponding to the gap in a direction from the element toward the antenna, when the developing device is mounted to the image forming apparatus main unit and the element performs wireless communication with the antenna.

In this case, an image forming system is realized, with which the amount of noise intruding into the gap between the element and the antenna is suitably reduced when wireless communication is performed between the element and the antenna.

====Seventh Invention=====

A cartridge including: (a) a communication unit including: a base; an antenna supported by the base; and an element supported by the base, the element being for communication via the antenna; and (b) a housing by which the communication unit is supported with the element being positioned on an upstream side of the base, with respect to a mounting direction in which it is mounted to the image forming apparatus main unit.

The upstream side, with respect to the mounting direction when mounting the cartridge into an image forming apparatus main unit, is the side of the person doing the mounting, and becomes the side opposite of the image forming apparatus main unit. That is to say, when mounting the cartridge to the image forming apparatus main unit, at least the base of the communication unit is present further downstream (on the side of the image forming apparatus main unit) than the element, so that the element is not positioned at the frontmost end of the cartridge. Therefore, when the cartridge is being mounted to the image forming apparatus main unit, there is little risk that the person doing the mounting damages it by inadvertently bumping it against the frame. That is to say, the user or the like can mount the cartridge without paying excessively close attention. Consequently, a cartridge can be realized that is easy to mount.

In the foregoing cartridge, it is preferable that the communication unit communicates with the image forming apparatus main unit via an apparatus-side antenna provided to the image forming apparatus main unit.

The communication unit communicates via an apparatus-side antenna, with which the image forming apparatus is provided, so that the communication unit and the apparatus-side antenna are provided at positions that are close to each other. Therefore, there is little space around the communication unit when the cartridge is mounted to the image forming apparatus main unit. However, when the cartridge is inserted, the position where the element passes has already been passed by the front end side of the cartridge, and a portion of the cartridge is supported by the image forming apparatus main unit, so that there is little risk of inadvertently damaging the element during the insertion.

In the foregoing cartridge, it is preferable that the cartridge includes a positioning section for positioning with respect to the image forming apparatus main unit on a downstream side in the mounting direction; and that the communication unit is arranged on the downstream side in the mounting direction.

In order to ensure a favorable communication state with the communication unit, it is necessary to suitably position the communication unit and the apparatus-side antenna. In a cartridge having a positioning section on the downstream side, with respect to the mounting direction, the relative position to the apparatus-side antenna can be positioned with greater precision when the communication unit is provided on the downstream side with respect to the mounting direction. However, on the most downstream side of the cartridge, it comes close to the image forming apparatus main unit in an instable state during mounting, so that the cartridge may easily bump into the image forming apparatus main unit. Therefore, a cartridge can be realized with which favorable communication conditions can be ensured and that is easy to mount, by arranging the communication unit on the downstream side with respect to the mounting direction and arranging the element on the upstream side, with respect to the mounting direction, in the communication unit.

45

In the foregoing cartridge, it is preferable that the base is fixed to the housing, and

the antenna and the element are supported by the base on the side of the base that is opposite to the housing and are covered by a film.

With such a cartridge, the base is fixed to the housing, so that the element is arranged on the surface of the cartridge. In this situation, if the element is arranged on the upstream side of the base, there is little risk that it is damaged during the mounting of the cartridge, so that it is not necessary to provide a cover with high rigidity or a thick cover or the like, and it is possible to protect it by covering it with a film. That is to say, only a film is present on the side of the element surface, so that there is no need to remove it by a certain distance from the apparatus-side antenna due to the cover or the like, and favorable communication conditions can be ensured.

In the foregoing cartridge, it is preferable that the image forming apparatus main unit includes: an opening through which the cartridge is inserted; and a guiding portion that guides the cartridge to a mounting position; wherein the element is passed through the opening and mounted after the guiding portion has been engaged when introducing the cartridge from the opening.

With such a cartridge, the cartridge is mounted to the image forming apparatus main unit through the opening, but as the element with which the cartridge is provided passes the opening, the cartridge is engaged by the guiding portion. That is to say, when the element passes the opening, the cartridge is guided by a guiding portion at a location that is further downstream, with respect to the mounting direction, than the element, so that a stable state is attained. Therefore, the element that is introduced through the opening is moved into the image forming apparatus main unit in a stable state, so that it is possible to prevent that the element is damaged during the mounting of the cartridge.

In the foregoing cartridge, the cartridge may be a developing device in which a developer is contained inside the housing.

With such a cartridge, there is little risk that the element is damaged during mounting, and it is possible to realize a developing device that is easy to mount.

In the foregoing cartridge, the cartridge may be an image bearing member unit provided with an image bearing member that bears a latent image.

With such a cartridge, there is little risk that the element is damaged during mounting, and it is possible to realize an image bearing member unit that is easy to mount.

Furthermore, it may be a developing device (c) including: (a) a communication unit including: a base; an antenna supported by the base; and an element supported by the base, the element being for communication via the antenna; (b) a housing by which the communication unit is supported with the element being positioned on an upstream side of the base, with respect to a mounting direction in which it is mounted to the image forming apparatus main unit; wherein (d) the communication unit communicates with the image forming apparatus main unit via an apparatus-side antenna provided to the image forming apparatus main unit; (e) which includes a positioning section for positioning with respect to the image forming apparatus main unit on a downstream side in the mounting direction, wherein the communication unit is arranged on the downstream side in the mounting direction; (f) wherein the base is fixed to the housing; and the antenna and the element are supported by the base on the side of the base that is opposite to the housing and are covered by a film; (g) wherein the image forming apparatus main unit includes: an opening through which the cartridge is inserted; and a

46

guiding portion that guides the cartridge to a mounting position; wherein the element is passed through the opening and mounted after the guiding portion has been engaged when introducing the cartridge from the opening; (h) wherein a developer is contained inside the housing.

With such a developing device, all of the above-mentioned effects are displayed, so that the object of the present invention is attained most effectively.

10 Furthermore, it is also possible to realize an image forming apparatus including an image bearing member that bears a latent image and a developing device including the following (a) and (b): (a) a communication unit including: a base; an antenna supported by the base; and an element supported by the base, the element being for communication via the antenna; (b) a housing by which the communication unit, with the element being positioned on an upstream side of the base, is supported, with respect to a mounting direction in which it is mounted to the image forming apparatus main unit.

20 Furthermore, it is also possible to realize an image forming system including a computer and an image forming apparatus connected to the computer and including the following (A) and (B): (A) an image bearing member that bears a latent image, and (B) a developing device including the following (a) and (b): (a) a communication unit including: a base; an antenna supported by the base; and an element supported by the base, the element being for communication via the antenna; (b) a housing by which the communication unit, with the element being positioned on an upstream side of the base, is supported, with respect to a mounting direction in which it is mounted to the image forming apparatus main unit.

—Eighth Invention—

It may also be (d) an image forming apparatus including: 35 (a) a mounting section that is to be mounted with a cartridge provided with an element unit having a first antenna and an element; (b) an antenna unit including a second antenna for communicating with the first antenna, the antenna unit being arranged at a position that is spaced by a predetermined distance L from the first antenna of the cartridge mounted into the mounting section; (c) a communication region in which no conductive members are present besides the element unit, the antenna unit and a wire connected to the antenna unit, within a distance of L from the first antenna and within a distance of L from the second antenna.

With such an image forming apparatus, no conductive members are present in the communication region apart from the element unit, the antenna unit and a wire connected to the antenna unit, so that no parts obstructing the communication between the element unit and the antenna unit are present in the communication region. Therefore, it is possible to realize an image forming apparatus, with which favorable communication between the element unit and the antenna unit is possible.

55 In the foregoing image forming apparatus, it is preferable that the image forming apparatus includes a holder made of resin, the holder including a flexible tongue; and that the antenna unit is fixed via the holder by engaging the base supporting the second antenna with the tongue.

With such an image forming apparatus, the antenna unit is engaged by a tongue of the holder, which is made of resin, so that the antenna unit can be fixed to the image forming apparatus via the holder without providing conductive members 60 within the communication region. That is to say, no metal holder or screws are used, so that it is possible to accomplish favorable communication between the element unit and the

antenna unit. Furthermore, the tongue with which the antenna unit is engaged is flexible, so that it is easy to install the antenna unit in the holder.

In the foregoing image forming apparatus, it is preferable that the image forming apparatus includes a metal shielding member outside of the communication region.

Such an image forming apparatus has a metal shielding member outside of the communication region so that it is possible to block electromagnetic waves or the like, which may intrude into the communication region, from the communication region. Therefore, it is possible to ensure more favorable conditions for the communication between the element unit and the antenna unit. Moreover, the electromagnetic waves caused by the communication between the element unit and the antenna unit can be blocked with the shielding member, so that it is possible to prevent that the electromagnetic waves caused by the communication between the element unit and the antenna unit influence the operation of the image forming apparatus.

In the foregoing image forming apparatus, it is preferable that the shielding member is an apparatus shielding member for blocking the image forming apparatus with respect to the outside.

With such an image forming apparatus, the shielding member provided outside of the communication region is an apparatus shielding member, so that it is possible to ensure favorable communication conditions between the element unit and the antenna unit by blocking the electromagnetic waves intruding from outside the apparatus, without using a separate shielding member. Furthermore, it is possible to prevent that the electromagnetic waves caused by the communication between the element unit and the antenna unit are emitted out of the apparatus.

In the foregoing image forming apparatus, it is preferable that the image forming apparatus includes a power source and a power source shielding member covering the power source; and that the shield is used as the power source shielding member.

With such an image forming apparatus, the shielding member that is provided outside of the communication region is a power source shielding member, so that it is possible to prevent that the communication between the element unit and the antenna unit is disturbed by electromagnetic waves emitted from the power source. Moreover, it is possible to prevent that the electromagnetic waves generated by the communication between the element unit and the antenna unit affect the power source.

In the foregoing image forming apparatus, it is preferable that the cartridge is a developing device containing a developer for developing the latent image.

With such an image forming apparatus, it is possible to realize an image forming apparatus, in which the antenna unit of the image forming apparatus main unit and the element unit of the developing device can communicate under favorable conditions.

In the foregoing image forming apparatus, the cartridge may be an image bearing member unit including an image bearing member for bearing the latent image.

With such an image forming apparatus, it is possible to realize an image forming apparatus, in which the antenna unit of the image forming apparatus main unit and the element unit of the developing device can communicate under favorable conditions.

Furthermore, it may be an image forming apparatus including: (a) a mounting section that is to be mounted with a cartridge provided with an element unit including a first antenna and an element; (b) an antenna unit having a second

antenna for communicating with the first antenna, the antenna unit being arranged at a position that is spaced by a predetermined distance L from the first antenna of the cartridge mounted into the mounting section; (c) a communication region in which no conductive members are present besides the element unit, the antenna unit and a wire connected to the antenna unit, within a distance of L from the first antenna and within a distance of L from the second antenna; (d); (e) a holder made of resin, the holder including a flexible tongue, wherein the antenna unit is fixed via the holder by engaging the base supporting the second antenna with the tongue; and (f) a metal shielding member outside of the communication region; (g) the shielding member being an apparatus shielding member for blocking the image forming apparatus with respect to the outside; (h) the image forming apparatus including a power source and a power source shielding member covering the power source, the shield being used as the power source shielding member; and (i) the cartridge being a developing device containing a developer for developing a latent image.

With such an image forming apparatus, it is possible to realize an image forming apparatus that is superior to the prior art, since it includes a developing device that is capable of suitable communication with the image forming apparatus main unit.

Furthermore, it may be (C) an image forming system including: (A) a computer; and (B) an image forming apparatus including the following (a) to (i): (a) a mounting section that is to be mounted with a cartridge provided with an element unit including a first antenna and an element; (b) an antenna unit having a second antenna for communicating with the first antenna, the antenna unit being arranged at a position that is spaced by a predetermined distance L from the first antenna of the cartridge mounted into the mounting section; (c) a communication region in which no conductive members are present besides the element unit, the antenna unit and a wire connected to the antenna unit, within a distance of L from the first antenna and within a distance of L from the second antenna; (d); (e) a holder made of resin, the holder including a flexible tongue, wherein the antenna unit is fixed via the holder by engaging the base supporting the second antenna with the tongue; and (f) a metal shielding member outside of the communication region; (g) the shielding member being an apparatus shielding member for blocking the image forming apparatus with respect to the outside; (h) the image forming apparatus includes a power source and a power source shielding member covering the power source, the shield being used as the power source shielding member; and (i) the cartridge is a developing device containing a developer for developing a latent image.

With such an image forming system, it is possible to realize an image forming system that is superior to the prior art, because it includes a developing device that is capable of suitable communication with the image forming apparatus main unit.

—Ninth Invention—

It may also be a developing device including: a developing container containing a developer including a magnetic material; a container-side antenna that is provided at the developing container, and that is for communicating in a contactless manner, when mounted to an apparatus main unit, with a main unit-side antenna of the apparatus main unit; an intrusion prevention section for preventing intrusion of the developer into a predetermined region between the container-side antenna and the developer.

With such a developing device, an intrusion prevention section is provided for preventing intrusion of the developer into a predetermined region between the container-side antenna and the developer, which contains a magnetic material, so that it is possible to prevent magnetic material from entering into the predetermined region between the container-side antenna and the developer. That is to say, the developer is spaced apart by a predetermined region in which the magnetic material included at least in the developer is not present between the developer and the container-side antenna. Therefore, the magnetic flux generated by either the main unit-side antenna or the container-side antenna can pass through this predetermined region and reach a wider range. Therefore, the magnetic flux generated by either the main unit-side antenna or the container-side antenna can reliably reach the other antenna, so that favorable communication is possible.

In the foregoing developing device, it is preferable that the intrusion prevention section is a partitioning member for forming a gap by partitioning the predetermined region.

With such a developing device, the predetermined region is partitioned by the intrusion prevention section, so that it is possible to reliably ensure a region where no magnetic material is present, without the developer entering the predetermined region. Therefore, it is possible to ensure favorable communication between the main unit-side antenna and the container-side antenna.

In the foregoing developing device, the intrusion prevention member may be a region holding member that is provided such that it fills out the predetermined region.

With such a developing device, the predetermined region is filled out by the region holding member, so that no magnetic material enters the predetermined region. Thus, it is possible to ensure favorable communication between the main unit-side antenna and the container-side antenna.

In the foregoing developing device, it is preferable that the region holding member is a block made of urethane. With such a developing device, the region holding member is a block, so that it can be provided easily, for example by adhering it inside the developing container. Furthermore, since it is made of urethane, the region holding member is of light weight, and is particularly suited for a developing device that can be mounted and dismounted.

In the foregoing developing device, it is preferable that the container-side antenna and the main unit-side antenna communicate at positions spaced apart by a distance L ; and the predetermined region includes a region of a distance L from the container-side antenna, and is wider than that region.

With such a developing device, the predetermined region includes a region of a distance L from the container-side antenna, and is wider than that region, so that the magnetic flux generated by the container-side antenna reaches at least a region of the distance L also on the opposite side of the developing container with respect to the container-side antenna. Therefore, it is possible to let the magnetic flux reach up to the main unit-side antenna that is provided at a spacing of the distance L from the container-side antenna, and to let the magnetic flux generated by the main unit-side antenna reach the container-side antenna. Therefore, it is possible to accomplish favorable communication between the main unit-side antenna and the container-side antenna.

Furthermore, it may be a developing device including: a developing container containing a developer including a magnetic material; a container-side antenna that is provided at the developing container, and that is for communicating contactlessly, when mounted to an apparatus main unit, with a main unit-side antenna of the apparatus main unit; an intru-

sion prevention section for preventing intrusion of the developer into a predetermined region between the container-side antenna and the developer; wherein the intrusion prevention section is a partitioning member for forming a gap by partitioning the predetermined region; the container-side antenna and the main unit-side antenna communicate at positions spaced apart by a distance L ; and the predetermined region includes a region of a distance L from the container-side antenna, and is wider than that region.

10 With such a developing device, all of the above-mentioned effects can be displayed, so that the object of the present invention is attained most effectively.

Furthermore, (c) an image forming apparatus can be realized that includes: (a) an image bearing member that bears a latent image; and (b) a developing device including: a developing container containing a developer including a magnetic material; a container-side antenna that is provided at the developing container, and that is for communicating in a contactless manner, when mounted to an apparatus main unit, with a main unit-side antenna of the apparatus main unit; and an intrusion prevention section for preventing intrusion of the developer into a predetermined region between the container-side antenna and the developer.

15 Furthermore, (C) an image forming system can be realized that includes: (A) a computer; and (B) an image forming apparatus including the following (a) and (b): (a) an image bearing member that bears a latent image; and (b) a developing device including: a developing container containing a developer including a magnetic material; a container-side antenna that is provided at the developing container, and that is for communicating in a contactless manner, when mounted to an apparatus main unit, with a main unit-side antenna of the apparatus main unit; an intrusion prevention section for preventing intrusion of the developer into a predetermined region between the container-side antenna and the developer.

====Tenth Invention====

It may also be (d) an image forming apparatus including: (a) a mounting section that is to be mounted with a cartridge so that it can be mounted and dismounted; (b) a duct serving as an air passageway within an apparatus including the mounting section; and (c) a second antenna provided to the duct, the second antenna being for communicating with an element provided with the cartridge, via a first antenna provided to the cartridge.

20 With such an image forming apparatus, the duct provided inside the apparatus is an air passageway, so that the duct and the inside of the duct are cooled by an air-flow. Also the second antenna, which is provided in the duct, is cooled, and a temperature increase of the second antenna is suppressed. That is to say, by providing the second antenna in the duct, it is cooled and its temperature is kept from increasing, so that it is possible to ensure favorable communication between the image forming apparatus and the cartridge.

25 In the foregoing image forming apparatus, it is preferable that the second antenna is provided inside the duct. With such an image forming apparatus, the second antenna is provided inside the duct, so that the second antenna is directly cooled by the air-flow inside the duct, so that the second antenna can be cooled efficiently.

30 In the foregoing image forming apparatus, it is preferable that the second antenna is provided at an inner wall of the duct. With such an image forming apparatus, the second antenna is provided at an inner wall of the duct, so that it is not necessary to provide a separate member for fixing the second antenna. Therefore, it is possible to cool the second antenna

51

efficiently by directly exposing it to the air-flow, while reducing the number of parts and the number of man-hours for assembly.

In the foregoing image forming apparatus, the second antenna also may be provided at an outer wall of the duct. With such an image forming apparatus, the duct is cooled by the air-flow inside the duct, so that the second antenna, which is provided on an outer wall of the duct, can be cooled via the duct. Moreover, since the second antenna is provided on the outer wall of the duct, there is no wall portion constituting the duct between the second antenna and the first antenna. Therefore, compared to the case that the second antenna is provided inside the duct, the second antenna and the first antenna can be arranged closer to each other, so that they are arranged at a distance at which favorable communication is possible, and the second antenna can be cooled via the duct, thus enabling favorable communication.

In the foregoing image forming apparatus, it is preferable that upstream, with respect to the direction of the air flow, from an antenna placement part where the second antenna is arranged, the duct has a part with a cross-sectional area that is larger than a cross-sectional area in a direction intersecting with the direction of the air flow at the antenna placement location.

With this image forming apparatus, upstream from the antenna placement location, there is a location with a cross-sectional area that is larger than a cross-sectional area in a direction intersecting with the direction of the air flow at the antenna placement location, so that the air-flow inside the duct becomes faster at the antenna placement location. Therefore, the second antenna, which is arranged at the antenna placement location, can be cooled even more efficiently, due to the faster air-flow.

In the foregoing image forming apparatus, it is preferable that the duct is made of resin. With such an image forming apparatus, since the duct is made of resin, that is, of a non-conductive member, the second antenna is not blocked and can communicate favorably with the first antenna even if the second antenna is provided in the duct.

In the foregoing image forming apparatus, it is preferable that the duct is an exhaust duct for exhausting air inside the apparatus to outside of the apparatus.

With such an image forming apparatus, by providing the second antenna in the exhaust duct, the second antenna can be cooled by utilizing the air flow for exhausting the air inside the apparatus out of the apparatus.

In the foregoing image forming apparatus, it is preferable that a filter is provided upstream of the second antenna, with respect to the direction of the air flow inside the duct.

With such an apparatus, it is possible to prevent dust, dirt and the like within the apparatus from adhering to the second antenna. In this situation, if conductive substances, such as iron dust or the like, are present in the dust or dirt inside the apparatus, then there is the risk that favorable communication between the first antenna and the second antenna is not possible. However, a filter is provided upstream of the second antenna, so that by preventing the iron dust or the like from adhering to the second antenna, it is possible to maintain favorable communication conditions.

In the foregoing image forming apparatus, it is preferable that a latent image borne on the image bearing member is developed using a developer; and the filter is provided in order to scavenge the developer.

With this image forming apparatus, it is possible to prevent the developer from scattering inside the apparatus, to cool the second antenna, and to ensure favorable communication between the image forming apparatus and the cartridge.

52

In the foregoing image forming apparatus, the developer may be a toner.

With this image forming apparatus, it is possible to prevent toner from scattering inside the apparatus, and to ensure favorable communication between the image forming apparatus and the cartridge, by cooling the second antenna.

In the foregoing image forming apparatus, it is preferable that the image forming apparatus includes an antenna driving circuit connected to the second antenna, that is for achieving communication between the first antenna and the second antenna; wherein the antenna driving circuit is provided at the duct.

With this image forming apparatus, it is possible to cool also the antenna driving circuit with the air-flow inside the duct.

Furthermore, it may be an image forming apparatus including: (a) a mounting section that is to be mounted with a cartridge removably; (b) a duct serving as an air passageway within an apparatus including the mounting section; and (c) a second antenna, with which the duct is provided, the second antenna being for communicating with an element with which the cartridge is provided, via a first antenna with which the cartridge is provided; wherein the second antenna is provided inside the duct; upstream, with respect to the direction of the air flow, from an antenna placement location where the second antenna is arranged, the duct has a location with a cross-sectional area that is larger than a cross-sectional area in a direction intersecting with the direction of the air flow at the antenna placement location; the duct is made of resin; the duct is an exhaust duct for exhausting air inside the apparatus out of the apparatus; a filter is provided upstream of the second antenna, with respect to the direction of the air flow inside the duct; a latent image borne on the image bearing member is developed using a developer; the upstream side opening is provided on the side of the image bearing member; the filter is provided in order to scavenge the developer; the developer is a toner; the image forming apparatus includes an antenna driving circuit that is connected to the second antenna and that is for achieving communication between the first antenna and the second antenna; and the antenna driving circuit is provided at the duct.

With such an image forming apparatus, all of the above-mentioned effects can be displayed, so that the object of the present invention is attained most effectively.

Furthermore, it is also possible to realize (C) an image forming system including: (A) a computer, and (B) an image forming apparatus including the following (a) to (c): (a) a mounting section that is to be mounted with a cartridge so that it can be mounted and dismounted; (b) a duct serving as an air passageway within an apparatus including the mounting section; (c) a second antenna provided to the duct, the second antenna being for communicating with an element provided to the cartridge, via a first antenna provided to the cartridge.

==Eleventh Invention==

A developing unit that can be mounted to and dismounted from an image forming apparatus main unit, the developing unit including: a memory unit including a memory; a label on which information relating to the developing unit is written, and that has been stuck to the developing unit so as to cover the memory unit.

With the foregoing developing unit, it is possible to effectively prevent the destruction of the memory unit without increasing the number of components.

Furthermore, the memory unit may be able to communicate wirelessly with the image forming apparatus main unit side, when the developing unit is mounted to the image forming apparatus main unit.

In this case, it is possible to effectively prevent the destruction of the memory unit, which can communicate wirelessly with the image forming apparatus main unit side, without increasing the number of parts.

Furthermore, the developing unit may be mounted to the image forming apparatus main unit by inserting it into the image forming apparatus main unit; and the memory unit may be provided on a downstream side, with respect to the insertion direction, of the developing unit.

In this case, when the developing unit is mounted or dismounted, the user or the like does not tend to touch the memory unit, and consequently, it is possible to effectively prevent the destruction of the memory unit.

Furthermore, the memory unit may be provided on a housing of the developing unit; and the label may be stuck to a surface of the housing so as to cover the memory unit.

Furthermore, the memory unit may be adhered to a surface of the housing.

In this case, it is not only possible to display the effect that the label effectively prevents the destruction of the memory unit without increasing the number of parts, but also the effect of effectively preventing that the memory unit is peeled off from the housing, due to the developer entering between the rear surface of the memory unit and the surface of the housing.

Furthermore, the housing may include an indentation; the memory unit may be adhered to a surface of the indentation; and the label may be stuck to a portion of the housing outside of the indentation.

In this case, since the memory unit is accommodated in the indentation, the user does not tend to touch the memory unit, so that the destruction of the memory unit can be prevented more effectively.

Furthermore, a maximum thickness of the memory unit may be smaller than a minimum depth of the indentation.

In this case, since the memory unit is entirely accommodated in the indentation, the user does not tend to touch the memory unit, so that the destruction of the memory unit can be prevented more effectively.

Furthermore, an air layer may be formed between a rear surface of the label and a surface of the memory unit on the side opposite to the adhesive surface.

In this case, the air layer functions as a cushion, so that the destruction of the memory unit can be suitable prevented, even in the case that the label is pressed down by the user or the like.

Furthermore, the developing unit may also include a cushion material between a rear surface of the label and a surface of the memory unit on the side opposite to the adhesive surface.

In this case, the cushion material functions as a cushion, so that the destruction of the memory unit can be suitable prevented, even in the case that the label is pressed down by the user or the like.

Furthermore, the information may be information representing warning messages relating to the handling of that developing unit. Furthermore, the information may be information cautioning persons handling that developing unit. Furthermore, the information may be information indicating a supplier of that developing unit. Furthermore, a developer may be contained in the developing unit; and the information may be information indicating the color of the developer. Furthermore, the developing unit may be mounted to the

image forming apparatus main unit by insertion into the image forming apparatus main unit; and the information may be information indicating an inserting direction of the developing unit.

Furthermore, the information may be information indicating that persons handling the developing unit must not grasp the developing unit at a portion to which the label has been stuck.

In this case, the possibility is reduced that persons handling the developing unit, such as a user or the like, touch the memory unit, and it becomes possible to prevent the destruction of the memory unit more effectively.

Furthermore, information may be written that urges persons handling the developing unit to grasp the developing unit at a portion other than the portion to which the label has been stuck.

In this case, the possibility is reduced that persons handling the developing unit, such as a user or the like, touch the memory unit, and it becomes possible to prevent the destruction of the memory unit more effectively.

Furthermore, it is possible to realize a developing unit that can be mounted to and dismounted from an image forming apparatus main unit, the developing unit including: a memory unit including a memory; a label on which information relating to the developing unit is written, and that has been stuck to the developing unit so as to cover the memory unit; wherein the memory unit can communicate wirelessly with the image forming apparatus main unit side, when the developing unit is mounted to the image forming apparatus main unit; the developing unit is mounted to the image forming apparatus main unit by inserting it into the image forming apparatus main unit; the memory unit is provided on a downstream side, with respect to the insertion direction, of the developing unit; the memory unit is provided on a housing of the developing unit;

the label is stuck to a surface of the housing, covering the memory unit; the memory unit is adhered to a surface of the housing; the housing includes an indentation; the memory unit is adhered to a surface of the indentation; the label is stuck to a portion of the housing outside of the indentation; a

maximum thickness of the memory unit is smaller than a minimum depth of the indentation; an air layer is formed between a rear surface of the label and a surface of the memory unit on the side opposite to the adhesive surface; the information is information representing warning messages relating to the handling of that developing unit; the information is information cautioning persons handling that developing unit; the information is information indicating a supplier of that developing unit; a developer is contained in the developing unit; the information is information indicating the color of the developer; and the information is information indicating an inserting direction of the developing unit.

This way, almost all of the above-mentioned effects can be displayed, so that the object of the present invention is attained most effectively.

Furthermore, it is possible to realize an image forming apparatus including: an image forming apparatus main unit; and a developing unit that can be mounted to and dismounted from the image forming apparatus main unit, the developing unit including: a memory unit including a memory; and a label on which information relating to the developing unit is written, and that has been stuck to the developing unit so as to cover the memory unit.

With the foregoing image forming apparatus, it is possible to effectively prevent the destruction of memory unit, without increasing the number of parts.

Furthermore, it is also possible to realize an image forming system including: a computer; and an image forming appa-

ratus that can be connected to the computer, the image forming apparatus including: an image forming apparatus main unit; and a developing unit that can be mounted to and dismounted from an image forming apparatus main unit, and that includes: a memory unit including a memory; and a label on which information relating to the developing unit is written, and that has been stuck to the developing unit so as to cover the memory unit.

With the foregoing image forming system, it is possible to effectively prevent the destruction of memory unit, without increasing the number of parts.

Furthermore, it is also possible to realize a photoconductor unit that can be mounted to and dismounted from an image forming apparatus main unit, the photoconductor unit including: a memory unit including a memory; and a label on which information relating to the developing unit is written, and that has been stuck to the developing unit so as to cover the memory unit.

With the foregoing photoconductor unit, it is possible to effectively prevent the destruction of memory unit, without increasing the number of parts.

Outline Of Image Forming Apparatus Of First Embodiment

Referring to FIGS. 1 to 5, an overview of a laser beam printer (hereinafter, also referred to as "printer") 10 serving as an example of an image forming apparatus is described. FIG. 1 is a diagram illustrating how developing containers 51, 52, 53 and 54 are mounted to and dismounted from a printer main unit 10a. FIG. 2 is a diagram showing the main structural components constituting the printer 10. FIG. 3 is a block diagram showing the control unit 100 of the printer 10. FIG. 4 is a perspective view of a developing container holding unit 50. FIG. 5 is a diagram showing the developing container holding unit 50 in a state in which a yellow developing container 54 is mounted to a mounting and dismounting section 50d. It should be noted that FIG. 2 is a diagram of a cross section taken perpendicular to the X direction in FIG. 1. Also, the vertical direction is indicated by arrows in FIG. 1 and FIG. 2, and for example, a paper supply tray 92 is disposed at a lower part of the printer 10 and a fixing unit 90 is disposed at an upper part of the printer 10.

Mounting and Dismounting Configuration

Developing containers 51, 52, 53 and 54, which are examples of developing devices, and a photoconductor unit 75 can be mounted to and dismounted from a printer main unit 10a, which is an example of an image forming apparatus main unit. The printer 10 is configured by mounting the developing containers 51, 52, 53 and 54 and the photoconductor unit 75 to the printer main unit 10a.

The printer main unit 10a has a first opening cover 10b that can be opened and closed, a second opening cover 10c that can be opened and closed and that is provided further inward than the first opening cover 10b, a photoconductor unit mounting and dismounting opening 10d through which the photoconductor unit 75 can be mounted and dismounted, and a developing container mounting and dismounting opening 10e through which the developing containers 51, 52, 53 and 54 can be mounted and dismounted.

Here, by opening the first opening cover 10b, the user can mount and dismount the photoconductor unit 75 with respect to the printer main unit 10a through the photoconductor unit mounting and dismounting opening 10d. Furthermore, by opening the second opening cover 10c, the user can mount and dismount the developing containers 51, 52, 53 and 54 with respect to the printer main unit 10a through the developing container mounting and dismounting opening 10e.

Configuration of the Printer 10

The configuration of the printer 10 in a state in which the developing containers 51, 52, 53 and 54 and the photoconductor unit 75 are mounted to the printer main unit 10a is described.

As shown in FIG. 2, the printer 10 according to the present embodiment includes a charging unit 30, an exposing unit 40, a developing container holding unit 50, a primary image transfer unit 60, an intermediate image transfer member 70, and a cleaning blade 76. These units are arranged along the rotation direction of a photoconductor 20, which is an example of an image bearing member bearing a latent image. The printer 10 further includes a secondary image transfer unit 80, a fixing unit 90, a display unit 95 constituted by a liquid-crystal panel and serving as a means for giving notifications to the user, and a control unit 100 for controlling these units and managing the operations of the printer.

The photoconductor 20 has a hollow cylindrical conductive base and a photoconductive layer formed on the outer circumferential surface of the conductive base, and is rotatable around its center axis. In the present embodiment, the photoconductor 20 rotates clockwise, as indicated by the arrow in FIG. 2.

The charging unit 30 is a device for charging the photoconductor 20. The exposing unit 40 is a device for forming a latent image on the charged photoconductor 20 by irradiating a laser beam thereon. The exposing unit 40 includes, for example, a semiconductor laser, a polygon mirror, and an F-θ lens, and irradiates a modulated laser beam onto the charged photoconductor 20 in accordance with image signals that have been input from a host computer, not shown in the drawings, such as a personal computer or a word processor.

The developing container holding unit 50 is a device for developing the latent image formed on the photoconductor 20 using toner T, which is an example of a developer contained in developing containers 51, 52, 53 and 54, that is, black (K) toner contained in a black developing container 51, magenta (M) toner contained in a magenta developing container 52, cyan (C) toner contained in a cyan developing container 53, and yellow (Y) toner contained in a yellow developing container 54.

The developing container holding unit 50 includes four mounting and dismounting sections 50a, 50b, 50c and 50d, with respect to which the developing containers 51, 52, 53 and 54 can be mounted and dismounted, arranged in intervals of 90° in the circumferential direction. That is to say, the developing container holding unit 50 is provided with the mounting and dismounting section 50a with respect to which the black developing container 51 can be mounted and dismounted, the mounting and dismounting section 50b with respect to which the magenta developing container 52 can be mounted and dismounted, the mounting and dismounting section 50c with respect to which the cyan developing container 53 can be mounted and dismounted, and the mounting and dismounting section 50d with respect to which the yellow developing container 54 can be mounted and dismounted. The developing container holding unit 50 is provided with a rotation shaft 50e, and the mounting and dismounting sections 50a, 50b, 50c and 50d can be shifted through the rotation of this rotation shaft 50e.

In this embodiment, the position of the four developing containers 51, 52, 53 and 54 can be moved by shifting the mounting and dismounting sections 50a, 50b, 50c and 50d. That is to say, the four developing containers 51, 52, 53 and 54 can be rotated around the rotation shaft 50e while maintaining their relative positions. Then, when the developing containers 51, 52, 53 and 54 are mounted to the mounting and dismount-

ing sections **50a**, **50b**, **50c** and **50d** and are moved to the developing position through the movement of the mounting and dismounting sections **50a**, **50b**, **50c** and **50d**, the latent image carried by the photoconductor **20** is developed with the toner contained in the respective developing containers **51**, **52**, **53** and **54**. It should be noted that details of the developing containers are discussed later.

Moreover, as shown in FIG. 4, the mounting and dismounting sections **50a**, **50b**, **50c** and **50d** are each provided with coupling holes **59** into which coupling protrusions provided on a coupling member **590** (explained later) of the respective developing containers can be fitted. For example, as shown in FIG. 5, coupling pins **595a** (explained later), which are an example of a coupling protrusion provided on the coupling member **590** of the yellow developing container **54** are fitted into the coupling holes **59** provided in the mounting and dismounting section **50d**. Moreover, as shown in FIG. 5, the mounting and dismounting sections **50a**, **50b**, **50c** and **50d** are each provided with springs **576**, which bias the developing container in the longitudinal direction. For example, the springs **576** provided on the mounting and dismounting section **50d** bias the yellow developing container **54** in its longitudinal direction. Moreover, as shown in FIG. 4, the mounting and dismounting sections **50a**, **50b**, **50c** and **50d** are each provided with a positioning hole **58** into which a positioning pin **588** (explained later) provided to the respective developing containers can be fitted. For example, a positioning pin **588** provided on the yellow developing container **54** can be fitted into the positioning hole **58** provided on the mounting and dismounting section **50d**.

The primary image transfer unit **60** is a device for transferring a single color toner image formed on the photoconductor **20** to the intermediate image transfer member **70**. When the four toner colors are successively transferred over one another, a full color toner image is formed on the intermediate image transfer member **70**. This intermediate image transfer member **70** is an endless belt that is rotatively driven at substantially the same circumferential velocity as the photoconductor **20**.

The secondary image transfer unit **80** is a device for transferring a single color toner image or a full color toner image formed on the intermediate image transfer member **70** to a recording medium such as paper, film, or cloth. The fixing unit **90** is a device for fusing the single color toner image or the full color toner image that has been transferred to the recording medium on the recording medium, such as paper, making it a permanent image.

The cleaning blade **76** is made of rubber and is in contact with the surface of the photoconductor **20**. The cleaning blade **76** scrapes off and removes toner remaining on the photoconductor **20**, after the toner image has been transferred to the intermediate image transfer body **70** by the primary image transfer unit **60**.

The photoconductor unit **75** is provided between the primary image transfer unit **60** and the exposing unit **40**, and includes the photoconductor **20**, the charging unit **30**, the cleaning blade **76**, and a waste toner container not shown in the drawings containing toner that has been scraped away by the cleaning blade **76**.

The control unit **100** is made of a main controller **101** and a unit controller **102**, as shown in FIG. 3. An image signal is input into the main controller **101**, and in accordance with a command based on this image signal, the unit controller **102** controls the various units, for example, to form the image.

Operation of the Printer **10**

The operation of the printer **10** configured as above is described below, referring to other structural components thereof as well.

First, when an image signal from a host computer not shown in the drawings is input into the main controller **101** of the printer **10** via an interface (I/F) **112**, the photoconductor **20**, developing rollers **510** provided in the developing containers **51**, **52**, **53** and **54**, and the intermediate image transfer member **70** are rotated under the control of the unit controller **102** based on a command from the main controller **101**. While rotating, the photoconductor **20** is successively charged by the charging unit **30** at a charging position.

The region of the photoconductor **20** that has been charged is brought to an exposure position through rotation of the photoconductor **20**, and a latent image corresponding to image information of a first color, for example yellow **Y**, is formed at that region by the exposing unit **40**. Moreover, the developing container holding unit **50** positions the yellow developing container **54** containing the yellow (**Y**) toner at the developing position opposite the photoconductor **20**.

The latent image formed on the photoconductor **20** is brought to a developing position through the rotation of the photoconductor **20**, and is developed with yellow toner by the yellow developing container **54**. Thus, a yellow toner image is formed on the photoconductor **20**.

The yellow toner image that is formed on the photoconductor **20** is brought to the primary image transfer position through rotation of the photoconductor **20** and is transferred to the intermediate image transfer member **70** by the primary image transfer unit **60**. At this time, a primary image transfer voltage of a polarity that is opposite the toner charge polarity is applied to the primary image transfer unit **60**. It should be noted that throughout this operation, the secondary image transfer unit **80** is removed from the intermediate image transfer member **70**.

The above process is repeated for a second color, a third color, and a fourth color, thereby transferring toner images of four colors corresponding to various image signals layered over one another onto the intermediate image transfer member **70**. Thus, a full color toner image is formed on the intermediate image transfer member **70**.

The full color toner image that is formed on the intermediate image transfer member **70** is brought to the secondary image transfer position through the rotation of the intermediate image transfer member **70** and is transferred to a recording medium by the secondary image transfer unit **80**. It should be noted that the recording medium is carried from the paper supply tray **92** to the secondary image transfer unit **80** via a paper supply roller **94** and registration rollers **96**. Also, when performing the image transfer operation, the secondary image transfer unit **80** is pressed against the intermediate image transfer member **70** while applying a secondary image transfer voltage to it.

The fixing unit **90** heats and applies pressure to the full color toner image that has been transferred to the recording medium, thus fusing it to the recording medium. On the other hand, after the photoconductor **20** has passed the primary image transfer position, the toner adhering to its surface is scraped off by the cleaning blade **76** and it is provided with a charge for forming the next latent image. The toner that is scraped off is collected in the waste toner container.

Overview of the Control Unit

The configuration of the control unit **100** is described next, with reference to FIG. 3. The control unit **100** includes the main controller **101** and the unit controller **102**.

The main controller 101 includes a CPU 111, an interface 112 for connection to a computer not shown in the drawings, an image memory 113 for storing image signals input from the computer, and a main controller-side memory 114 made of an EEPROM 114a that can be rewritten electrically, a RAM 114b, and a program ROM or the like in which a program for the various kinds of control is stored.

The CPU 111 of the main controller 101 controls the reading in and the reading out of image data that has been input via the interface into the image memory 113, and performs the control of the overall apparatus in synchronization with the CPU 120 of the unit controller 102 based on the control signals input from the computer.

The unit controller 102 includes the CPU 120, a unit controller-side memory 116 including an EEPROM 116a that can be rewritten electrically, a RAM, and a program ROM or the like in which a program for the various kinds of control is stored, as well as drive control circuits or the like for performing drive control of the various units of the entire device (the charging unit 30, the exposing unit 40, the developing container holding unit 50, the primary image transfer unit 60, the photoconductor unit 75, the secondary image transfer unit 80, the fixing unit 90 and the display unit 95).

The CPU 120 of the unit controller 102 is electrically connected to the various drive control circuits and controls the various drive control circuits in accordance with control signals from the CPU 111 of the main controller 101. That is to say, while the state of the units is detected by receiving signals from sensors or the like provided in each of the units, the units are controlled in accordance with signals input from the main controller 101.

Also, the CPU 120 provided in the unit controller 102 is connected to a non-volatile storage element (hereinafter, also referred to as "main unit-side memory") 122 such as a serial EEPROM via the serial interface (I/F) 121. This main unit-side memory 122 stores data that is necessary for the control of the apparatus.

Furthermore, the CPU 120 is capable of wirelessly communicating with elements 51a, 52a, 53a, and 54a, which are respectively provided in the developing containers 51, 52, 53, and 54, via the serial interface 121, a send-receive circuit 123, and a main unit-side antenna 124. During the wireless communication, the main unit-side antenna 124 writes information to the elements 51a, 52a, 53a, and 54a provided in the developing containers 51, 52, 53, and 54, respectively. The main unit-side antenna 124 is also capable of reading information from the elements 51a, 52a, 53a, and 54a provided in the developing containers 51, 52, 53, and 54, respectively.

Overview of the Developing containers

The configuration and operation of the developing containers 51, 52, 53, and 54 is explained next, using FIG. 6 to FIG. 10. FIG. 6 is a perspective view of the yellow developing container 54. FIG. 7 is a cross-sectional view showing the main structural components of the yellow developing container 54. FIG. 8 is a perspective view of a developing roller 510 provided with rolls 574. FIG. 9 is a front view of the coupling member 590. FIG. 10 is a perspective view showing the rear side of the coupling member 590. It should be noted that the cross-sectional view in FIG. 7 shows a cross section of the yellow developing container 54 taken along a plane that is perpendicular to the longitudinal direction shown in FIG. 6. Moreover, in FIG. 7, like in FIG. 1, the vertical direction is indicated by arrows, and for example, the center axis of the developing roller 510 is lower than the center axis of the photoconductor 20. Also, in FIG. 7, the yellow developing container 54 is shown positioned at a developing position that is in opposition to the photoconductor 20.

The black developing container 51 containing black (K) toner, the magenta developing container 52 containing magenta (M) toner, the cyan developing container 53 containing cyan (C) toner and the yellow developing container 54 containing yellow (Y) toner can be mounted to the developing container holding unit 50, but since the configuration and the operation of each of the developing containers is the same, explanations are given only for the yellow developing container 54 in the following.

10 Internal Configuration of the Yellow Developing Container 54

First, the configuration of the yellow developing container 54 is described. The yellow developing container 54 includes the developing roller 510, which is an example of a developer bearing member, a toner containing section 530, a housing 540 containing toner T, a toner supply roller 550, a regulating blade 560, a sealing member 520, a positioning shaft (also referred to as "positioning pin" in this embodiment) 588 serving as an example of a positioning member and a coupling member 590.

The developing roller 510 bears toner T and carries it to the developing position opposite the photoconductor 20, and develops the latent image carried by the photoconductor 20 with the toner T carried to the developing position. This developing roller 510, which is made of metal, is fabricated from an aluminum alloy, such as 5056 aluminum alloy or 6063 aluminum alloy, or an iron alloy such as STKM, and may be nickel-plated or chromium-plated if necessary. As shown in FIG. 8, the developing roller 510 includes a large-diameter section 510a and axle sections 510b.

Moreover, as shown in FIG. 6, the developing roller 510 is supported by the housing 540 at its two ends in longitudinal direction, that is, at the axle section 510b, and can be rotated around its center axis. As shown in FIG. 7, the developing roller 510 rotates in a direction (the counterclockwise direction in FIG. 7) that is opposite to the rotation direction of the photoconductor 20 (the clockwise direction in FIG. 7). Its center axis is lower than the center axis of the photoconductor 20.

40 Also, as shown in FIG. 7, in a state where the yellow developing container 54 is in opposition to the photoconductor 20, there is a gap between the developing roller 510 and the photoconductor 20. That is to say, the yellow developing container 54 develops the latent image formed on the photoconductor 20 in a noncontacting manner. It should be noted that during the development of the latent image formed on the photoconductor 20, an alternating electric field is formed between the developing roller 510 and the photoconductor 20.

45 Furthermore, as shown in FIG. 8, rolls 574, which are an example of distance holding members, are formed on both ends in longitudinal direction of the developing roller 510. When the developing containers 51, 52, 53 and 54 are positioned in the developing position, these rolls 574 have the function of coming into contact with the photoconductor 20 and thereby holding a distance between the photoconductor 20 and the developing roller 510. The rolls 574 are supported by the axle sections 510b. The outer diameter of the rolls 574 is larger than the outer diameter of the large-diameter section 510a. Therefore, the rolls 574 are able to hold a distance between the photoconductor 20 and the developing roller 510.

50 The sealing member 520 prevents the toner T in the yellow developing container 54 from leaking to the outside, and also collects toner T on the developing roller 510, after it has passed the developing position, into the developing container without scraping it off. This sealing member 520 is a seal

made of polyethylene film or the like. The sealing member 520 is supported by a seal support metal plate 522, and is attached to the housing 540 via the seal support metal plate 522. Furthermore, a seal biasing member 524 made of Moltopren or the like is provided on the side of the sealing member 520 that is opposite to its developing roller 510 side, and due to the elasticity of the seal biasing member 524, the sealing member 520 is pressed against the developing roller 510. It should be noted that the contact position where the sealing member 520 contacts the developing roller 510 is above the center axis of the developing roller 510.

The housing 540 is fabricated by welding together a plurality of integrally molded housing sections, namely an upper housing section 542 and a lower housing section 544. A partitioning wall 545 for partitioning the toner T that protrudes (vertically in FIG. 7) from the inner wall to the inside partitions the inside of the housing 540 into two toner containing sections 530, namely a first toner containing section 530a and a second toner containing section 530b. It should be noted that the housing 540 has a housing opening 572 at its bottom, and is arranged such that a portion of the developing roller 510 is exposed in this housing opening 572. Moreover, an element 54a is attached to the housing 540. The configuration of this element 54a and the position at which it is attached to the housing 540 are explained later.

Attachment protrusions 581a and 581b (see FIG. 9) are provided on a side wall 547 of the housing 540 at the other end side in the longitudinal direction. The attachment protrusion 581a can be fitted into an attachment hole 593a of the later-explained coupling member 590, and the attachment protrusion 581b can be fitted into an attachment hole 593b of the coupling member 590. The attachment protrusions 581a and 581b have a circular cross section.

Moreover, the toner containing section 530 may be provided with a stirring member for stirring the toner T, but in the present embodiment, the developing containers (the black developing container 51, the magenta developing container 52, the cyan developing container 53 and the yellow developing container 54) rotate with the rotation of the developing container holding unit 50, and this stirs the toner T inside the developing containers, so that the toner containing section 530 is not provided with a stirring member.

The toner supply roller 550 is provided in the above-mentioned first toner containing section 530a and not only supplies toner T that is contained in this first toner containing section 530a to the developing roller 510, but also scrapes off, from the developing roller 510, toner T that has remained on the developing roller 510 after developing. The toner supply roller 550 is made of polyurethane foam, for example, and abuts against the developing roller 510 in a state of elastic deformation. The toner supply roller 550 is disposed at the bottom of the toner containing section 530, and the toner T contained in the containing section 530 is supplied to the developing roller 510 by this toner supply roller 550 at the bottom of the toner containing section 530. The toner supply roller 550 rotates in a direction (the clockwise direction in FIG. 6) that is opposite the rotation direction of the developing roller 510 (the counterclockwise direction in FIG. 6). Its center axis is lower than the rotation center axis of the developing roller 510.

The regulating blade 560 applies a charge to the toner T borne on the developing roller 510 and regulates the layer thickness of the toner T borne on the developing roller 510. The regulating blade 560 includes a rubber part 560a and rubber supporting part 560b. The rubber part 560a is made of silicone rubber or urethane rubber, for example, and the rubber supporting part 560b is a thin plate of phosphor bronze or

stainless steel, for example, and has elasticity. The rubber part 560a is supported by the rubber supporting part 560b, and the rubber supporting part 560b is attached to the housing 540 via a blade support metal plate 562, with one end of the rubber supporting part 560b being supported by the blade support metal plate 562. Also, a blade backing member 570 made of Moltopren or the like is provided on the side of the regulating blade 560 that is opposite the side of the developing roller 510.

10 Here, the rubber part 560a is pressed against the developing roller 510 by the elastic force due to the bending of the rubber supporting part 560b. The blade backing member 570 prevents the toner T from entering in between the rubber supporting part 560b and the housing 540, and stabilizes the 15 elasticity due to the bending of the rubber supporting part 560b while pressing the rubber part 560a against the developing roller 510 by urging the rubber part 560a toward the developing roller 510 from directly behind the rubber part 560a. Consequently, the blade backing member 570 makes 20 the contact of the rubber part 560a with the developing roller 510 more uniform.

The end of the regulating blade 560 on the side opposite the side supported by the blade support metal plate 562, that is, its front end, is not in contact with the developing roller 510, and 25 a portion thereof removed from this front end by a predetermined distance is in contact with the developing roller 510 over a certain width. That is to say, the regulating blade 560 does not come into contact with the developing roller 510 at its edge but rather at a mid section thereof. Also, the regulating blade 560 is disposed such that its front end is facing upstream with respect to the direction in which the developing roller 510 rotates, and is in so-called counter contact. It 30 should be noted that the contact position where the regulating blade 560 contacts the developing roller 510 is below the center axis of the developing roller 510 and is below the center axis of the toner supply roller 550.

Configuration of the Positioning Member

The following is a description of the configuration of the 40 positioning pin 588. As shown in FIG. 6, the positioning pin 588 is provided on one end in longitudinal direction of the yellow developing container main unit, which is an example of a developing device main unit. It should be noted that “yellow developing container main unit” refers to those parts of the yellow developing container 54 excluding the positioning pin 588, the coupling member 590 and the element 54a.

This positioning pin 588 has the function of positioning the yellow developing container main unit with respect to the mounting and dismounting section 50d by engaging the mounting and dismounting section 50d, or more specifically 50 by fitting into the positioning hole 58 provided on the mounting and dismounting section 50d, as shown in FIG. 5, when the yellow developing container 54 is mounted to the mounting and dismounting section 50d.

55 Moreover, the positioning pin 588, which is made of metal, is arranged such that its axial direction extends in the longitudinal direction of the developing container main unit. One end of the positioning pin 588 is fixed to a side wall 546 on one side in longitudinal direction of the housing 540. The other end of the positioning pin 588 is tapered, so that it can 60 be easily fitted into the positioning hole 58 of the mounting and dismounting section.

Configuration of the Coupling Member

The configuration of the coupling member 590 is described 65 next. As shown in FIG. 6, the coupling member 590 is attached to the other end side in the longitudinal direction of the yellow developing container main unit.

As shown in FIG. 10, the coupling member 590 is provided with coupling pins 595a and 595b, which are an example of coupling protrusions that can be fitted into the coupling holes 59 of the mounting and dismounting section 50d. When the yellow developing container 54 is mounted to the mounting and dismounting section 50d, the coupling pins 595a and 595b are fitted into the coupling holes 59 provided in the mounting and dismounting section 50d. Thus, when the yellow developing container 54 is mounted to the mounting and dismounting section 50d, the coupling member 590 is coupled to the mounting and dismounting section 50d. It should be noted that when the coupling member 590 is coupled to the mounting and dismounting section 50d, the movement of the coupling member 590 with respect to the mounting and dismounting section 50d is restricted.

Furthermore, as shown in FIG. 9, the coupling member 590 includes an attachment hole 593a into which the attachment protrusion 581a provided on the side wall 547 on the other end in longitudinal direction of the housing 540 can be fitted, and an attachment hole 593b into which the attachment protrusion 581b can be fitted. When the attachment protrusion 581a is fitted into the attachment hole 593a and the attachment protrusion 581b is fitted into the attachment hole 593b, the coupling member 590 is attached to the side wall on the other end side in the longitudinal direction of the housing 540, by stopping screws 598 via the coupling member 590 with respect to screw holes provided in the attachment protrusion 581a and the attachment protrusion 581b, as shown in FIG. 5.

Moreover, as shown in FIG. 9, the attachment hole 593a and the attachment hole 593b have an elliptical cross section. The attachment hole 593a and the attachment hole 593b are provided such that the directions of the major axes of the elliptical cross sections are the same direction. Moreover, as noted above, the cross section of the attachment protrusion 581a is circular. Consequently, the attachment hole 593a allows movement of the attachment protrusion 581a, which is fitted into the attachment hole 593a, within the attachment hole 593a. Similarly, the attachment hole 593b allows movement of the attachment protrusion 581b, which is fitted into the attachment hole 593b, within the attachment hole 593b.

That is to say, the attachment hole 593a allows movement of the attachment protrusion 581a within the attachment hole 593a in the direction of the major axis of its elliptical cross section, and the attachment hole 593b allows movement of the attachment protrusion 581b within the attachment hole 593b in the direction of the major axis of its elliptical cross section. It should be noted that the movement of the attachment protrusion 581a within the attachment hole 593a and the movement of the attachment protrusion 581b within the attachment hole 593b occur at the same timing. Thus, the coupling member 590 is attached in such a manner that its relative position to the developing container main unit can be changed.

Operation of the Yellow Developing Container 54

Next, the operation of the yellow developing container 54 is described. In the yellow developing container 54 configured in this manner, the toner T that is contained in the toner containing section 530 is supplied to the developing roller 510 by rotating the toner supply roller 550.

As the developing roller 510 rotates, the toner T that is supplied to the developing roller 510 is brought to the contact position of the regulating blade 560, and when it passes that contact position, the layer thickness of the toner T is regulated, and a charge is applied to it. The toner T on the developing roller 510, whose layer thickness has been regulated and which has been charged, is brought to the developing position in opposition to the photoconductor 20 by further

rotation of the developing roller 510, and is supplied for the development of the latent image formed on the photoconductor 20 in an alternating electric field at the developing position.

5 The toner T on the developing roller 510 that has passed the developing position due to further rotation of the developing roller 510 passes the upper sealing member 520 and is collected in the developing device without being scraped off by the upper sealing member 520. Moreover, the toner T that still 10 remains on the developing roller 510 is stripped off by the toner supply roller 550.

The Developing Position, Communication Position and Mounting and Dismounting Position of the Developing Containers

15 As mentioned above, the developing containers 51, 52, 53 and 54 are moved together with the movement of the mounting and dismounting sections 50a, 50b, 50c and 50d. At that time, the mounting and dismounting sections are moved such that the developing containers are positioned in predetermined positions. Such predetermined positions are the developing position, serving as a first position, the communication position, serving as a second position, and the mounting and dismounting position. Since the developing position, the communication position and the mounting and dismounting 20 position of each of the developing containers are the same, the developing position, the communication position and the mounting and dismounting position of the yellow developing container 54 are explained in the following with reference to FIGS. 11A to 11D. FIG. 11A is a diagram showing the developing container holding unit 50 in a state where the yellow developing container 54 is positioned at the developing position. FIG. 11B is a diagram showing the developing container holding unit 50 in a state where the yellow developing container 54 is positioned at the communication position. FIG. 25 30 35 11C is a diagram showing the developing container holding unit 50 in a state where the yellow developing container 54 is positioned at the mounting and dismounting position. FIG. 11D is a diagram showing a state where the developing container holding unit 50 is positioned in its home position.

40 In the state shown in FIG. 11A, the yellow developing container 54 is positioned at the developing position in which the developing roller 510 is in opposition to the photoconductor 20. In this state, the developing roller 510 is able to develop the latent image borne on the photoconductor 20. In 45 the state in which the yellow developing container 54 is positioned in the developing position, as noted above, the springs 576 provided in the mounting and dismounting section 50d bias the yellow developing container main unit in its longitudinal direction. Due to this spring force of the springs 576, the rolls 574 come into contact with the photoconductor 20. It should be noted that when the photoconductor 20 is 50 installed in a slanted manner with respect to the printer main unit 10a, then the yellow developing container main unit moves with respect to the coupling member 590 when the yellow developing container 54 is positioned in the developing position, that is, the attachment protrusion 581a of the yellow developing container main unit moves in the major axis direction within the attachment hole 593a of the coupling member and the attachment protrusion 581b of the yellow 55 developing container main unit moves in the major axis direction within the attachment hole 593b of the coupling member 590, so that the rolls 574 with which the yellow developing container main unit is provided abut suitably against the photoconductor 20. During this, the relative position of the developing container main unit and the coupling member 590 is 60 65 changed in accordance with the spring force of the springs 576. It should be noted that in a state in which the yellow

developing container **54** is positioned in the developing position, the magenta developing container **52** is positioned in the communication position.

Furthermore, when the developing container holding unit **50** is rotated for a predetermined angle in Z-direction in FIG. 11A from the state shown in FIG. 11A around its rotation shaft **50e**, then the state shown in FIG. 11B is achieved. In the state shown in FIG. 11B, the yellow developing container **54** is positioned in the communication position. In this state, the element **54a** provided on the yellow developing container **54** opposes the main unit-side antenna **124** in a noncontacting manner. This element **54a** is capable of communication with the main unit-side antenna **124**. Furthermore, when the yellow developing container **54** is positioned in the communication position, the rolls **574** of the yellow developing container **54** do not come into contact with members on the side of the printer main unit **10a**. It should be noted that when the yellow developing container **54** is positioned in the communication position, the black developing container **51** is positioned in the developing position. Therefore, the communication between the main unit-side antenna **124** and the element can take place while the black developing container **51** develops the latent image borne on the photoconductor **20**.

Furthermore, when the developing container holding unit **50** is rotated around its rotation shaft **50e** for a predetermined angle in Z-direction in FIG. 11B from the state shown in FIG. 11B, then the state shown in FIG. 11C is achieved. In the state shown in FIG. 11C, the yellow developing container **54** is positioned in the mounting and dismounting position. In this state, the yellow developing container **54** can be mounted and dismounted via the developing container mounting and dismounting opening **10e**, that is, the yellow developing container **54** can be mounted to the mounting and dismounting section **50d** or it can be dismounted from the mounting and dismounting section **50d**.

It should be noted that after the power source of the printer main unit **10a** has been turned on and an initialization operation has been performed, and before the printer **10** forms an image, the developing container holding unit **50** is positioned in the home position shown in FIG. 11D.

Configuration of the Element

The configuration of the element provided in the developing container as well as the configuration for sending and receiving data is described next with reference to FIG. 12, FIG. 13 and FIG. 14. FIG. 12 is a plan transparent view showing the configuration of the element. FIG. 13 is a block diagram illustrating the internal configuration of the element and the send/receive section. FIG. 14 is a diagram illustrating the information stored in a memory cell **54h** of the element **54a**.

The developing containers **51**, **52**, **53** and **54** are each provided with an element, but the configuration of the elements provided in the developing containers and the positions at which the elements are attached to the developing container main units are the same, so that in the following, the element **54a** attached to the yellow developing container **54** is explained as an example.

When the yellow developing container **54** is mounted to the mounting and dismounting section **50d**, the element **54a** can communicate with the printer main unit **10a** in a noncontacting manner. As mentioned above, the yellow developing container **54** is moved together with the movement of the mounting and dismounting section **50d**. When the yellow developing container **54** has been moved to the communication position, which is different from the developing position, the element **54a** communicates in a noncontacting manner with the main unit-side antenna **124** with which the printer

main unit **10a** is provided. The element **54a** is provided further inward than the main unit-side antenna **124** with respect to the radial direction of the rotation of the developing container holding unit **50**. It should be noted that the main unit-side antenna **124** is provided such that its longitudinal direction (Y direction in FIG. 11B) extends in the rotation direction of the developing container holding unit **50** (Z direction in FIG. 11B).

As shown in FIG. 6, the element **54a** is provided between the positioning pin **588** and the coupling member **590** in the longitudinal direction of the yellow developing container main unit on the side of the positioning pin **588**, that is, on one side in longitudinal direction of the yellow developing container unit. More specifically, the element **54a** is provided near the side wall **546** at one end in the longitudinal direction of the yellow developing container main unit.

Moreover, the element **54a** is attached to an outer surface **543** of the housing **540**, which is provided extending in the longitudinal direction of the housing **540**. Here, the outer surface **543** refers to the part of the housing **540** corresponding to the dash-dotted line in FIG. 7. It should be noted that this outer surface **543** includes a circularly arc-shaped surface **543a**, whose cross section through a perpendicular plane that is perpendicular to the longitudinal direction of the housing **540** is circularly arc-shaped. This circularly arc-shaped surface **543a** is arranged such that its circular arc extends along the rotation direction of the developing container holding unit **50** when the yellow developing container **54** is mounted to the mounting and dismounting section **50d**. As shown in FIG. 7, the element **54a** is attached at a position of the circularly arc-shaped surface **543a** that is furthest removed from the developing roller **510**.

If the element **54a** and the main unit-side antenna **124** are in a predetermined positional relationship, for example, if they are within a distance of 10 mm of one another, information can be exchanged in a noncontacting manner between the two. The element **54a** is overall very compact and thin, and one of its sides is adhesive and can be adhered to an object as a seal. It is also called a memory tag, for example, and is commercially available in various forms.

As shown in FIG. 12, the element **54a** has a non-contact IC chip **54b**, a resonance capacitor **54c** that is formed by etching a metal film, and a flat coil serving as an antenna **54d**. These are mounted onto a plastic film and covered by a transparent cover sheet.

As shown in FIG. 13, the printer main unit **10a** includes a coil that serves as the main unit-side antenna **124**, the send-receive circuit **123**, and the serial interface **121**, which is connected to the controller (CPU) **120** of the printer main unit **10a**.

As shown in FIG. 13, the non-contact IC chip **54b** includes a rectifier **54e**, a signal analysis section RF (Radio Frequency) **54f**, a controller **54g**, and the memory cell **54h**. The memory cell **54h** is a non-volatile memory that can be electrically read and written, such as a NAND flash ROM, and is capable of storing information that has been written on it and reading stored information from the outside.

The antenna **54d** of the element **54a** and the main unit-side antenna **124** communicate wirelessly with one another, so that information stored in the memory cell **54h** can be read and information can be written to the memory cell **54h**. Also, the high-frequency signals that are generated by the send-receive circuit **123** of the printer main unit **10a** are induced as a high-frequency magnetic field via the main unit-side antenna **124**. This high-frequency magnetic field is absorbed via the antenna **54d** of the element **54a** and is rectified by the

rectifier 54e, thus serving as a DC power source for driving the circuits in the IC chip 54b.

The memory cell 54h of the element 54a stores various types of information, as shown in FIG. 14. The address 00H stores unique ID information for each element, such as the serial number of the element, the address 01H stores the date when the yellow developing container 54 was manufactured, the address 02H stores information for specifying the destination of the yellow developing container 54, the address 03H stores information for specifying the manufacturing line on which the yellow developing container 54 was manufactured, the address 04H stores information for specifying models with which the yellow developing container 54 is compatible, the address 05H stores remaining toner amount information as information indicating the amount of toner that is contained in the yellow developing container 54, and the address 06H and subsequent regions also store information as appropriate.

The ID information that is stored in the memory cell 54h of the element 54a can be written at the time that the storage element is manufactured in the factory. The printer main unit 10a can read this ID information to identify the individual elements 54a, 51a, 52a and 53a.

It should be noted that it is also possible to let the main unit-side antenna 124 communicate wirelessly with the element 54a not only when the developing container holding unit 50 is standing still but also when the developing container holding unit 50 is moving. That is, it is possible to make the main unit-side antenna 124 capable of communicating wirelessly with the element 54a even when the element 54a is moving.

Advantages of the Developing Container of the Present Embodiment

The developing devices according to the present embodiment, that is, the developing containers 51, 52, 53 and 54 that can be mounted and dismounted with respect to the mounting and dismounting sections 50a, 50b, 50c and 50d with which the printer main unit 10a (image forming apparatus main unit) is provided and that that include a developing container main unit (developing device main unit), the positioning pin 588 (positioning member) that is fixed on one end in the longitudinal direction of the developing container main units and is for positioning the developing container main units with respect to the mounting and dismounting sections by engaging the mounting and dismounting sections when the developing containers 51, 52, 53 and 54 are mounted to the mounting and dismounting sections 50a, 50b, 50c and 50d, a coupling member 590 that is attached to the other end in longitudinal direction of the developing container main units in such a manner that their relative position to the developing container main units is variable and that are coupled with the mounting and dismounting sections when the developing containers 51, 52, 53 and 54 are mounted to the mounting and dismounting sections 50a, 50b, 50c and 50d, and elements 51a, 52a, 53a and 54a that are provided on one end in longitudinal direction of the developing container main units and that can communicate with the printer main unit 10a in a noncontacting manner when the developing containers 51, 52, 53 and 54 are mounted to the mounting and dismounting sections 50a, 50b, 50c and 50d. Thus, developing containers 51, 52, 53 and 54 can be realized that can communicate suitably with the printer main unit 10a. This is described in greater detail in the following.

When the developing containers 51, 52, 53 and 54 are mounted to the mounting and dismounting sections 50a, 50b, 50c and 50d, the coupling member 590 coupled to the mounting and dismounting sections is attached to the developing

container main units in such a manner that its relative position to the developing container main units can be changed, so that depending on the position where the elements are attached to the developing container main units, the distance between the elements and the printer main unit 10a may change considerably with this change in relative position. In this case, there is the risk that the elements cannot communicate properly with the printer main unit 10a.

This is explained more specifically with a comparative example. Here, in the developing container of the comparative example, the element is provided at the other end side in the longitudinal direction of the developing container main unit, that is, on the side where the coupling member 590 is attached. The coupling member 590 is attached in such a manner that its relative position to the developing container main unit can be changed, in order to make it possible to achieve the desired distance between the photoconductor 20 and the developing container as the latent image borne on the photoconductor 20 is developed by the developing container, even when the photoconductor 20 is installed in a slanted manner with respect to the printer main unit 10a. Therefore, if the element is provided on the other side in longitudinal direction of the developing container main unit, that is, on the side where the coupling member 590 is attached, then there is the possibility that the distance between the printer main unit 10a and the element changes considerably as the relative position between the developing container main unit and the coupling member 590 changes. Then, if the distance between the printer main unit 10a and the element changes considerably, there is the risk that the element cannot communicate properly with the printer main unit 10a.

In the present embodiment on the other hand, the elements 51a, 52a, 53a and 54a are provided on the one end in the longitudinal direction of the developing container main units, as shown in FIG. 6. In this case, the elements are positioned on the side of the positioning pin 588. As noted above, the positioning pin 588 positions the developing container main unit with respect to the mounting and dismounting section, so that on this side in the longitudinal direction, changes in the distance between the developing container main units and the printer main unit 10a are less likely to occur. Moreover, even when there is a change in the relative position between the developing container main units and the coupling member 590 provided on the other side in the longitudinal direction, its influence on the one side in the longitudinal direction is small. Therefore, if the elements are provided on the one side in longitudinal direction of the developing container main units, that is, on the side of the positioning pin 588, then the distance between the elements attached to the developing container main units and the printer main unit 10a tends not to change. Consequently, the elements 51a, 52a, 53a and 54a can communicate properly with the printer main unit 10a.

Thus, if the developing containers 51, 52, 53 and 54 have elements 51a, 52a, 53a and 54a that are arranged on the one end in the longitudinal direction of the developing container main units, then the distance between the printer main unit 10a and the elements is less likely to change, so that it is possible to realize developing containers that can communicate properly with the printer main unit 10a.

Other Embodiments

An image forming apparatus or the like according to the present invention was explained by way of the foregoing embodiment, but the foregoing embodiment of the invention is merely for the purpose of elucidating the present invention and is not to be interpreted as limiting the present invention.

The invention can of course be altered and improved without departing from the gist thereof and equivalents are intended to be embraced therein.

In the foregoing embodiment, an intermediate image transfer type full-color laser beam printer was described as an example of the image forming apparatus, but the present invention can also be applied to various other types of image forming apparatuses, such as full-color laser beam printers that are not of the intermediate image transfer type, monochrome laser beam printers, copying machines, and facsimiles.

Also, in the foregoing embodiment, the photoconductor, which is an image bearing member, was explained as having a photoconductive layer on the outer circumferential surface of a hollow cylindrical conductive member, but there is no limitation to this. For example, it may also be a so-called photoconductive belt, in which a photoconductive layer is provided on the surface of a belt-shaped photoconductive member.

Furthermore, in the foregoing embodiment, as shown in FIG. 2 for example, the mounting and dismounting sections 50a, 50b, 50c and 50d are movable, and when the developing containers 51, 52, 53 and 54 are mounted to the mounting and dismounting sections and are moved to the developing position (first position) through the movement of the mounting and dismounting sections, then the latent image borne on the photoconductor 20 (image bearing member) provided in the printer main unit 10a is developed. Moreover, the elements 51a, 52a, 53a and 54a communicate in a noncontacting manner with the printer main unit 10a when the developing containers 51, 52, 53 and 54 have been moved to the communication position (second position), which is different from the developing position. However, there is no limitation to this. For example, it is also possible to let the developing containers not move at all.

However, if the developing containers 51, 52, 53 and 54 move together with the movement of the mounting and dismounting sections 50a, 50b, 50c and 50d, then the relative position between the developing container main units and the coupling member 590 changes more easily when the developing containers are positioned in the communication position than in the case that the developing containers do not move, so that there is a greater risk that the distance between the printer main unit 10a and the elements 51a, 52a, 53a and 54a changes. Therefore, the effect of providing the elements on the one end in the longitudinal direction of the developing container main units, that is, the effect that developing containers can be realized that can communicate properly with the printer main unit 10a is more advantageous in the case that the developing containers move together with the movement of the mounting and dismounting sections. For this reason, the above-described embodiment is more preferable.

Furthermore, as shown in FIG. 4, in the present embodiment, the mounting and dismounting sections 50a, 50b, 50c and 50d are each provided with springs 576, which bias the developing container main units in their longitudinal direction. Also, the relative position between the developing container main units and the coupling member 590 is changed in accordance with the biasing amount of the springs 576. However, there is no limitation to this. For example, it is also possible that the mounting and dismounting sections are not provided with springs biasing the developing container main units in their longitudinal direction.

However, if the mounting and dismounting sections 50a, 50b, 50c and 50d are provided with springs 576 that bias the developing container main units in their longitudinal direction, then the developing containers oscillate due to the

expansion and contraction of the springs 576 when the developing containers 51, 52, 53 and 54 are positioned in the communication position. Then, when the developing containers oscillate, there is the risk that the distance between the printer main unit 10a and the elements changes and that the elements cannot communicate properly with the printer main unit 10a. Therefore, the effect of providing the elements on the one end in the longitudinal direction of the developing container main units, that is, the effect that developing containers can be realized that can communicate properly with the printer main unit 10a can be more effectively displayed in the case that the mounting and dismounting sections are provided with springs 576. For this reason, the above-described embodiment is more preferable.

Furthermore, in the above-described embodiment, as shown in FIG. 8, the developing container main units include a developing roller 510 (developer bearing member) for bearing toner (developer) T developing the latent image borne on the photoconductor 20 with toner T, and rolls 574 (distance holding members) that are provided at both ends in the longitudinal direction of the developing rollers 510 and that are for holding a distance between the photoconductor 20 and the developing roller 510 by coming into contact with the photoconductor 20. Moreover, when the developing containers 51, 52, 53 and 54 are moved to the developing position, the rolls 574 hold this distance by coming into contact with the photoconductor 20. However, there is no limitation to this.

In order to properly develop the latent image carried on the photodetector 20, it is necessary to hold a proper distance between the developing roller 510 and the photodetector 20. To hold this distance, rolls 574 coming into contact with the photodetector 20 on both sides in longitudinal direction of the developing roller 510 may be provided. In this case, if the relative position between the developing container main unit provided with the developing roller 510 and the coupling member 590 can change, the rolls 574 can be abutted against the photoconductor 20 such that the developing roller 510 follows the photoconductor 20 even if the photoconductor 20 is attached at an inclination with respect to the printer main unit 10a, so that it becomes possible to hold a proper distance between the developing roller 510 and the photoconductor 20. For this reason, the above-described embodiment is more preferable.

Furthermore, in the above-described embodiment, as shown in FIG. 6, the positioning member is a positioning pin 588 (positioning shaft) that is fixed to the side wall 546 on one end in the longitudinal direction of the developing container main unit, such that its axial direction extends along the longitudinal direction of the developing container main unit. Moreover, as shown in FIG. 5, when the developing containers 51, 52, 53 and 54 are mounted to the mounting and dismounting sections 50a, 50b, 50c and 50d, the positioning pins 588 are fitted to the positioning holes 58 provided on the mounting and dismounting sections to position the developing container main units with respect to the mounting and dismounting sections. However, there is no limitation to this. For example, it is also possible that the positioning member positions the developing container main units with respect to the mounting and dismounting sections with a configuration different from positioning pins 588 fitted into positioning holes 58.

However, if the positioning pins 588 position the developing container main units with respect to the mounting and dismounting sections 50a, 50b, 50c and 50d by fitting into positioning holes 58, then the developing container main units can be positioned with respect to the mounting and

dismounting sections with a simple configuration. For this reason, the above-described embodiment is more preferable.

Furthermore, as shown in FIG. 4, in the present embodiment, the mounting and dismounting sections **50a**, **50b**, **50c** and **50d** are each provided with coupling holes **59**. Moreover, as shown in FIG. 10, the coupling member **590** is provided with coupling pins **595a** and **595b** (coupling protrusions) that can be fitted into the coupling holes **59**, and the coupling member **590** can be attached to the side wall **547** on the other end in longitudinal direction of the developing container main unit. Moreover, as shown in FIG. 5, when the developing containers **51**, **52**, **53** and **54** are mounted to the mounting and dismounting sections **50a**, **50b**, **50c** and **50d**, the coupling member **590** is coupled to the mounting and dismounting section by fitting the coupling pins **595a** and **595b** into the coupling holes **59**. However, there is no limitation to this. For example, it is also possible to couple the coupling member **590** with the mounting and dismounting section with another configuration than coupling the coupling pins **595a** into the coupling holes **59**.

However, if the coupling member **590** is coupled with the mounting and dismounting sections **50a**, **50b**, **50c** and **50d** by fitting the coupling pins **595a** and **595b** into the coupling holes **59**, then it is possible to couple the coupling member **590** with the mounting and dismounting sections with a simple configuration. For this reason, the above-described embodiment is more preferable.

Furthermore, as shown in FIG. 9, in the present embodiment, the developing container main units are provided with attachment protrusions **581a** and **581b** having a circular cross section. Moreover, the coupling member **590** is provided with attachment holes (**593a** into which the attachment protrusion **581a** can be fitted and **593b** into which the attachment protrusion **581b** can be fitted) which have an elliptical cross section and into which attachment protrusions can be fitted. Moreover, the attachment holes **593a** and **593b** allow some movement of the attachment protrusions fitted into those attachment holes within the attachment holes. However, there is no limitation to this. For example, it is also possible that the cross-sectional shape of the attachment holes **593a** and **593b** is a shape other than an elliptical shape.

Furthermore, as shown in FIG. 7, in the above-described embodiment, the developing container main units are provided with a housing **540** for containing the toner **T**. Moreover, as shown in FIG. 6, the elements **51a**, **52a**, **53a** and **54a** are each attached to the outer surface **543** of the housing **540**, which is provided extending along the longitudinal direction of the housing **540**. However, there is no limitation to this. For example, it is also possible to attach the elements to the side wall **546** on the one end in longitudinal direction of the developing container main unit, to which the positioning pin **588** is fixed.

Furthermore, in the above-described embodiment, as shown in FIG. 6, the developing container main unit is supported by the housing **540** at both ends in the longitudinal direction, and is provided with the developing roller **510** for bearing the toner **T** and developing the latent image borne on the photoconductor **20** with the toner **T**. Moreover, as shown in FIG. 7, the outer surface **543** of the housing **540** is provided with a circularly arc-shaped surface **543a**, whose cross section through a perpendicular plane that is perpendicular to the longitudinal direction of the housing **540** is circularly arc-shaped. As shown in FIG. 7, the elements **51a**, **52a**, **53a** and **54a** are attached at positions of the circularly arc-shaped surface **543a** that are furthest removed from the developing rollers **510**. However, there is no limitation to this. For example, it is also possible that the elements are attached at

positions of the circularly arc-shaped surface **543a** that are close to the developing rollers **510**.

However, if the elements **51a**, **52a**, **53a** and **54a** are attached at the positions of the circularly arc-shaped surface **543a** that are furthest removed from the developing rollers **510**, then it can be prevented that the toner **T** borne on the developing roller **510** is scattered and adheres to the elements, so that the elements can communicate more properly with the printer main unit **10a**. For this reason, the above-described embodiment is more preferable.

Configuration of Image Forming System Etc.

Next, an embodiment of an image forming system serving as an example of an embodiment of the present invention is described with reference to the drawings.

FIG. 15 is an explanatory diagram showing the external configuration of an image forming system. An image forming system **700** is provided with a computer **702**, a display device **704**, a printer **10**, input devices **708** and reading device **710**.

In this embodiment, the computer **702** is contained within a mini-tower type housing, but there is no limitation to this. A CRT (cathode ray tube), a plasma display, or a liquid crystal display device, for example, is generally used as the display device **704**, but there is no limitation to this. The printer **10** is the printer described above. In this embodiment, the input devices **708** are a keyboard **708A** and a mouse **708B**, but there is no limitation to these. In this embodiment, a flexible disk drive device **710A** and a CD-ROM drive device **710B** are used as the reading devices **710**, but there is no limitation to these, and the reading devices **710** may also include an MO (magneto-optical) disk drive device or a DVD (digital versatile disk), for example.

FIG. 16 is a block diagram showing the configuration of the image forming system shown in FIG. 15. An internal memory **802** such as a RAM is provided within the casing containing the computer **702**, and furthermore an external memory such as a hard disk drive unit **804** is provided.

In the above explanations, an example was given in which the image forming system is constituted by connecting the printer **10** to the computer **702**, the display device **704**, the input devices **708**, and the reading devices **710**, but there is no limitation to this. For example, the image forming system may also be made of the computer **702** and the printer **10**, and the image forming system does not have to be provided with any one of the display device **704**, the input devices **708**, and the reading devices **710**.

It is also possible that the printer **10** has some of the functions or mechanisms of the computer **702**, the display device **704**, the input devices **708**, and the reading devices **710**. As an example, the printer **10** may be configured so as to have an image processing section for carrying out image processing, a display section for carrying out various types of displays, and a recording media mounting and dismounting section into and from which recording media storing image data captured by a digital camera or the like are inserted and taken out.

As an overall system, the image forming system that is thus achieved is superior to conventional systems.

Overview of Image Forming Apparatus of Second Embodiment

The following is an explanation of a second embodiment of the present invention, with reference to the drawings. FIGS. 17 to 21 are diagram showing an embodiment of an image forming apparatus according to the present invention.

In FIG. 17 and FIG. 18, the image forming apparatus is a printer that is used by connecting it to an external device such

as a personal computer PC that creates and outputs images of text or the like. This image forming apparatus includes an image recording device 1010 that records and forms images on one side or both sides of recording paper (recording medium) through electrophotography by reading in image data of text or the like to be image-formed, a paper carrying device 1020 that carries a plurality of stacked recording papers to the image recording device 1010 and carries the recording paper on which an image has been recorded and formed out of the apparatus, stacking the recording paper, and a control unit 1030 that is connected to a personal computer PC and makes print-outs by forming images on the recording paper through comprehensive control of the overall apparatus including the image recording device 1010 and the paper carrying device 1020 in accordance with the image data that has been received.

Simply speaking, the image recording device 1010 includes, as shown in FIG. 17, a laser beam scanning device 1011 scanning a laser beam L1 based on image data, a photoconductive drum (bearing member) 1012 on the surface of which an electrostatic latent image is exposed and formed based on image data that is irradiated and scanned with the laser beam L1 from the laser beam scanning device 1011, a charge device 1013 charging the outer circumferential surface of the photoconductive drum 1012 such that an electrostatic latent image can be formed by irradiating the laser beam L1, a developing cartridge 1014 (shown only at one place) for each of the colors, which contains yellow (Y), cyan (C), magenta (M) or black (K) toner and performs toner development of the electrostatic latent image on the photoconductive drum 1012, a developing rotary unit 1015 holding the developing cartridges 1014 in preset spaces 1015a for each color and rotating them around a rotation shaft 1015b, an intermediate image transfer belt (intermediate image transfer medium) 1016, which can receive the toner image developed on the photoconductive drum 1012 so that a toner image (monochrome image or color image) is formed on it that can be transferred and recorded on recording paper, an image transfer roller 1017 transferring the toner image carried on the intermediate image transfer belt 1016 by applying a contact pressure (nip) such that the recording paper carried up to it is sandwiched between the image transfer roller 1017 and the intermediate image transfer belt 1016, and carrying the recording paper downstream while clamping the recording paper, a pair of fixing rollers 1018 fixing the toner image by applying heat and pressure to the recording paper onto which the toner image has been transferred and which has been carried up to them, and clamping and carrying the recording paper further downstream, and a waste toner tank 1019 collecting and storing toner that has remained on the photoconductive drum 1012 with a blade 1019a.

Thus, in the image recording device 1010, the developing cartridge 1014 inside the developing rotary unit 1015 that has been switched in accordance with the image data develops with toner the electrostatic latent image based on the image data formed on the surface of the photoconductive drum 1012 with the laser beam scanning device 1011. After that, the toner image on the photoconductive drum 1012 is transferred and recorded via the intermediate image transfer belt 1016 onto recording paper that has been carried with the paper carry device 1020, and then fixed by applying heat and pressure with the pair of fixing rollers 1018, thus accomplishing image formation. It should be noted that the intermediate image transfer belt 1016, the image transfer roller 1017 and the pair of fixing rollers 1018 of this image recording device also have the function of carrying the recording paper, so that they also constitute a part of the paper carry device 1020

explained below. Also the unit of the intermediate image transfer belt 1016 is provided with a waste toner tank in which the toner remaining on the belt 1016 is collected with a blade and stored.

Simply speaking, the paper carry device 1020 includes, as shown in FIG. 17, a paper cassette 1021, which is attachably and detachably set in a lower section of the apparatus main unit and in which a plurality of sheets of recording paper are stacked, a pick-up roller 1022, which picks up the uppermost recording paper by rotating while being pressed against the stack of recording paper that has been elevated with an elevating plate 1021a at the bottom surface of the paper cassette 1021, thereby feeding the recording paper to a carry path f, a pair of relay carry rollers 1023a and 1023b, which receive the recording paper that is fed to them by the pick-up roller 1022 and clamp and carry the recording paper to the carry path f further downstream, a pair of registration rollers 1024, which receive the recording paper in the carry path f that is carried by the pair of relay carry rollers 1023a and 1023b and clamp and carry the recording paper to an image recording formation position given by the intermediate image transfer belt 1016 and the image transfer roller 1017 of the image recording device 1010, and a pair of paper discharge rollers 1025a and 1025b, which receive the recording paper on one side of which a fixed image has been formed by carrying the recording paper along the carry path f from the pair of registration rollers 1024, between the intermediate image transfer belt 1016 and the image transfer roller 1017 and between the pair of fixing rollers 1018, and which carries out and discharges and stacks the recording paper on a paper discharge table 1029 on top of the apparatus main unit.

Thus, after the recording paper that has been picked up from the paper cassette 1021 with the pick-up roller 1022 has been passed on via the pair of relay carry rollers 1023a and 1023b to the pair of registration rollers 1024, the paper carry device 1020 supplies the recording paper to the image recording formation position at which the recording paper is pressed against by the intermediate image transfer belt 1016 and the image transfer roller 1017, such that the pair of registration rollers 1024 is synchronized with the operation of the image recording device 1010. The recording paper, on which the toner image on the intermediate image transfer belt 1016 has been transferred and recorded, and the image based on the image data has been fixed (recording formation) with the pair of fixing rollers 1018, is received by the pair of paper discharge rollers 1025a and 1025b and is carried out and discharged and stacked on the paper discharge table 1029.

It should be noted that this paper carry device 1020 includes a reverse carry path r and a pair of intermediate carry rollers 1027 disposed on this path r for turning over recording paper on one side of which an image has been formed and feeding it to the carry path f on the upstream side of the pair of registration rollers 1024. The recording paper, which has been fed into the reverse carry path r by inverting the rotation of the pair of paper discharge rollers 1025a and 1025b is received by the pair of intermediate carry rollers 1027 and passed on to the pair of registration rollers 1024, so that image formation on both sides of the recording paper is possible. Moreover, the paper carry device 1020 includes a manual feed path m and a pair of manual feed rollers 1028 disposed on this path m for manually feeding recording paper into the carry path f on the upstream side of the pair of registration rollers 1024. Image formation on one side or both sides of the recording paper is possible by receiving the recording paper inserted into this manual feed path m with the pair of manual feed rollers 1028 and passing it to the pair of registration rollers 1024.

As shown in FIG. 18, the control unit 1030 includes a controller section 1031 and an engine controller 1032 implemented on a circuit board mounted inside the apparatus main unit. These perform various kinds of data process control and drive control of the various components of the apparatus in accordance with a program that is provided in advance.

Simply speaking, the controller section 1031 exchanges various kinds of information, such as print commands, with a printer driver of a personal computer PC, with a CPU not shown in the drawings executing procedures of various processes in accordance with a processing program stored in a memory, receives image data, such as text, to be formed as an image (printed) on the recording paper, and temporarily stores the image data in a memory not shown in the drawings. Since the image data (image information signal) received from the personal computer PC is so-called RGB data of red (R), green (G) and blue (B), the controller section 1031 reads the data from the memory and passes it to the engine controller 1032 while converting this data into so-called YMCK image data of yellow (Y), magenta (M), cyan (C) and black (K) that can be printed.

With the CPU 1033 following the control program stored in the ROM 1034, the engine controller 1032 receives the image data page by page, for example, from the controller section 1031 and temporarily stores it in a main unit memory 1035, and an image based on this image data is formed on the recording paper by exchanging various kinds of information with the image recording device 1010 and the paper carry device 1020 while using a RAM 1036 as a working area. Moreover, when the CPU 1033 performs the image formation control at this time, it lets each component of the apparatus operate optimally by measuring the various processing times with an internal timer function (time measurement means) 1033a.

Thus, when the control unit 1030 receives image data from the personal computer PC or the like, the controller section 1031 outputs image data, which it has converted from RGB data to YMCK data, to the engine controller 1032, while temporarily storing the image data. In accordance with a control program in the ROM 1034, the CPU 1033 of the engine controller 1032 comprehensively controls the driving of the various sections of the apparatus while using the RAM 1036 as a working area, based on the image data from the controller section 1031 stored in units of pages in the main unit memory 1035. Due to this drive control, the paper carry device 1020 retrieves the recording paper from the paper cassette 1021 and carries it to the paper discharge table 1029, whereas the image recording device 1010 develops with toner the electrostatic latent image formed on the photoconductive drum 1012 with the developing cartridge 1014, based on the image data, so that the toner image is transferred and fixed on one or both sides of the recording paper that has been carried there, thereby accomplishing image formation.

It should be noted that in FIG. 18, an I/O interface 1037 is connected between the image recording device 1010, the paper carry device 1020 and the controller section 1031 on the one hand and the engine controller 1032 on the other hand, such that various kinds of information can be exchanged. A D/A converter 1038 and an A/D converter 1039 convert digital signals (D) into analog signals (A) and convert analog signals into digital signals, such that the various kinds of information that the engine controller 1032 exchanges with the image recording device 1010, the paper carry device 1020 and the controller section 1031 can be processed by these.

The developing cartridges 1014 of the image recording device 1010 are provided with a similar external shape, such that they can be accommodated in a plurality of storage posi-

tions that are partitioned by partitioning frames 1015c that rotate around the rotation shaft 1015b of the developing rotary unit 1015. Based on the print commands including the image data from the personal computer PC received by the 5 CPU (controller) 1033 of the engine controller 1032 via the controller section 1031, the developing rotary unit 1015 is rotated around the rotation shaft 1015b to switch the developing cartridge 1014 facing the photoconductive drum 1012, and the toner image to be formed is developed by transferring 10 and fixing toner on one side or both sides of the recording paper.

For example, by storing in the developing rotary unit 1015 developing cartridges 1014 containing toner of the colors yellow (Y), cyan (C), magenta (M) and black (K) and switching 15 the color of the toner for developing the electrostatic latent image on the photosensitive drum 1012, the image recording device 1010 can superimpose or select toner of various colors and print and form color images or monochrome images, based on the received image data.

Moreover, the image recording device 1010 can also perform image formation when toner of the same color is contained in all developing cartridges 1014 and those developing cartridges 1014 are mounted in the developing rotary unit 1015. For example, by mounting four developing cartridges 25 1014 containing toner of the same color black (K), it is possible to use the apparatus as a special purpose apparatus that successively switches the developing cartridges 1014 developing the electrostatic latent image on the photoconductive drum 1012 and continuously prints monochrome images.

30 A so-called memory tag 1041 that is overall very compact and thin is adhered to a predetermined outer surface of each of the developing cartridges 1014 by making one side of it adhesive. When the memory tag 1041 is moved to a rotation position (communication position) facing a main unit-side antenna 1051 on the main unit side of the apparatus shown in FIG. 17, then it is arranged at a position along an external cover 1100 of the apparatus main unit, or in other words, it is placed (adhered) on the outer surface of the developing cartridge 1014 such that it becomes closest to this external cover 40 1100. This memory tag 1041 is designed to store and hold necessary information and to pass the necessary information to the CPU 1033 of the engine controller 1032 by communicating in a noncontacting manner with a send-receive circuit 1052 on the apparatus main unit side via the main unit-side antenna 1051 to exchange various kinds of information. Here, 45 the main unit-side antenna 1051 on the apparatus main unit side, which is fabricated in substantially the same manner as the later-described developing-side antenna 1043, is placed within a distance of 10 mm of the memory tag 1041 at the communication position, for example, so as to be able to communicate in a noncontacting manner with the memory tag 1041. The main unit-side antenna 1051 is connected to a circuit board constituting the send-receive circuit 1052 and performing communication in a noncontacting manner with the memory tag 1041. This send-receive circuit 1052 is connected via the I/O interface 1037 to the CPU 1033 of the apparatus main unit side.

More specifically, as shown in FIG. 19(a), in the memory tag 50 1041 on the side of the developing cartridge 1014, a non-contact IC chip 1042 and the developing-side antenna 1043 are mounted on a plastic film and covered by a transparent cover sheet. The non-contact IC chip 1042 stores and holds various kinds of information based on commands from the send-receive circuit 1052 via the main unit-side antenna 1051 and reads necessary information from these various 55 kinds of information, passing on the relevant information to the send-receive circuit 1052. The developing-side antenna

1043 is made of a planar coil that is connected in parallel to the non-contact IC chip **1042** and a resonance capacitor **1043a** that is formed by etching a metal film. Thus, a high-frequency magnetic field induced via the main unit-side antenna **1051** by high-frequency signals generated with the send-receive circuit **1052** on the apparatus main unit side can be received (absorbed) by the developing-side antenna **1043** of the memory tag **1041** and input into the non-contact IC chip **1042**.

As shown in FIG. 19(b), the non-contact IC chip **1042** of the memory tag **1041** includes a rectifier **1044** serving as a DC power source that rectifies the high-frequency magnetic field (high-frequency signals) from the send-receive circuit **1052** on the apparatus main unit side received via the developing-side antenna **1043** and drives the various circuits within the chip, a signal analysis section RF (Radio Frequency) **1045**, which analyzes the high-frequency signals of the received high-frequency magnetic field and generates a high-frequency magnetic field that can be absorbed by the main unit-side antenna **1051** by generating a high-frequency signal based on the various kinds of signals to be passed on to the send-receive circuit **1052** on the apparatus main unit side and inputting this high-frequency signal to the developing-side antenna **1043**, a non-volatile memory cell **1046**, such as a NAND flash-ROM or the like, that can store and hold information written into it and from which this stored information can be read out from the outside, and a controller **1047**, which rewrites the information stored in the memory cell **1046** by exchanging various kinds of signals with the send-receive circuit **1052** on the side of the apparatus main unit via the signal analysis section RF **1045** and passes the stored information that has been read out to the send-receive circuit **1052**, while being driven by the DC power source of the interposed rectifier **1044**. That is to say, the memory cell **1046** constitutes a storage element and the non-contact IC chip **1042** in which this memory cell **1046** is incorporated constitutes a communication means on the side of the developing cartridge **1014** adjacent to the developing-side antenna **1043**, whereas the main unit-side antenna **1051** and the send-receive circuit **1052** constitute a communication means on the apparatus main unit side.

Here, stored and held inside the memory cell **1046** of the non-contact IC chip **1042** are unique ID information, such as a serial number for each memory tag **1041**, manufacturing information, such as the date when the developing cartridge **1014** was manufactured or the manufacturing number, destination information specifying the destination of the developing cartridge **1014**, model information specifying models to which the developing cartridge **1014** can be mounted, toner information, such as information on the color and the remaining amount of toner contained in the developing cartridge **1014**, and various kinds of necessary information, such as the number of recycles or the number of times the developing cartridge **1014** has been mounted and dismounted. Thus, the engine controller **1032** of the control unit **1030** can perform an optimal image formation control, by suitably ascertaining various kinds of information that the CPU **1033** has stored and held in the main unit memory **1035**, such as the presence and the position of the developing cartridge **1014** in the storage position of the developing rotary unit **1015**, or information about the color of the toner of the developing cartridge **1014**. Moreover, if an error occurs, the various kinds of information can be useful in finding the cause of the error by displaying and outputting the information to an operation port.

The information stored in the memory cell **1046** of the non-contact IC chip **1042** is rewritten and read out by per-

forming communication in a noncontacting manner between the CPU **1033** of the engine controller **1032** and the memory tag **1041** via the send-receive circuit **1052** in accordance with a control program in the ROM **1034**. For example, when the power is turned on or when the developing cartridge **1014** is exchanged, the CPU **1033** lets the developing rotary unit **1015** rotate at least one turn such that the memory tag **1041** (developing-side antenna **1043**) of each developing cartridge **1014** faces the main unit-side antenna **1051** for the time necessary for communication in a noncontacting manner, to perform a rewrite and read-out process.

During regular operation, as shown in FIG. 20 for example, when the CPU **1033** receives a print command of image data, by beginning with the rotation of the developing rotary unit **1015** from the home position, which is the stand-by position, first the developing cartridge **1014Y** containing the yellow (Y) toner is positioned in the image recording formation position P facing the photoconductive drum **1012**, and the electrostatic latent image formed on the surface of the photoconductive drum **1012** is developed with toner by this developing cartridge **1014Y**. After that, the CPU **1033** successively positions (switches) the developing cartridge **1014C** containing cyan (C) toner, the developing cartridge **1014M** containing magenta (M) toner and the developing cartridge **1014K** containing black (K) toner in a similar manner at the image recording formation position P, and forms color toner images based on the image data by letting them carry out toner development so as to transfer and fix the toner image on the recording paper, thus print-processing the image data.

Since, parallel to this print control, the memory tag **1041Y** of the yellow (Y) developing cartridge **1014Y** that has carried out the immediately preceding development operation is positioned in the communication position facing the main unit-side antenna **1051** while the cyan (C) developing cartridge **1014C** performs the development operation, the CPU **1033** rewrites and reads out the information stored in the memory cell **1046** of this memory tag **1041Y** by performing contactless information with this memory tag **1041Y** via the send-receive circuit **1052** on the apparatus main unit side. After this, since the memory tag **1041C** of the cyan (C) developing cartridge **1014C** and the memory tag **1041M** of the magenta (M) developing cartridge **1014M** are successively positioned in the communication position facing the main unit-side antenna **1051** during the development operation of the magenta (M) developing cartridge **1014M** and the black (K) developing cartridge **1014K**, the CPU **1033** rewrites and reads out the information stored in the memory cells **1046** of these memory tags **1041C** and **1041M** by performing contactless information with these memory tags **1041C** and **1041M** via the send-receive circuit **1052** on the apparatus main unit side. Then, after the development operation with the black (K) developing cartridge **1014K** has finished, the CPU **1033** positions the yellow (Y) developing cartridge **1014Y** again in the image recording formation position P without performing an image formation process, so that the memory tag **1041K** of the black (K) developing cartridge **1014K** is positioned in the communication position facing the main unit-side antenna **1051** and communication in a noncontacting manner is carried out with this memory tag **1041K** via the send-receive circuit **1052** on the apparatus main unit side. Thus, the CPU **1033** finishes the rewriting and reading of the information stored in the memory cells **1046** of all memory tags **1041Y** to **1041K**, after which it rotates the developing rotary unit **1015** to its home position to put it into the stand-by state.

In this situation, the memory tag 1041 of the developing cartridge 1014 in the communication position facing the main unit-side antenna 1051 is positioned on the upper side, closest to the external cover 1100, sandwiching the developing rotary unit 1015 (the developing cartridge 1014) between it and the image recording formation position P facing the photoconductor drum 1012. Therefore, the memory tag 1041 in the communication position is removed from the vicinity of the photoconductive drum 1012, which is a source of noise while the charge voltage is applied, and since the developing rotary unit 1015 and the developing cartridge 1014 are disposed between the memory tag 1041 and the photoconductive drum 1012, the information stored in the memory cell 1046 can be rewritten and read out without errors, unaffected by the noise. Moreover, the memory tag 1041 in the communication position is furthest removed from the pair of fixing rollers 1018 and the laser beam scanning device 1011, which are heat-generating members, and is positioned, via the external cover 1100, in an environment that is closest to the external temperature, so that with the elements in the non-contact IC chip 1042 being as little influenced by heat as possible, it is possible to carry out communication in a noncontacting manner with the send-receive circuit 1052 on the apparatus main unit side efficiently (without a drop in processing speed or the like) and the information stored in the memory cell 1046 can be rewritten and read out without errors.

Moreover, through synchronized rotation of the developing roller 1014a facing the surface of the photoconductive drum 1012 via a gap, the developing cartridge 1014 performs toner development by transferring toner and letting it adhere to the electrostatic latent image formed on that surface. The photoconductive drum 1012 rotates clockwise in FIG. 17, whereas the developing roller 1014a rotates counterclockwise in FIG. 17, so that a small fraction of the toner that is about to be transferred from the developing roller 1014a to the photoconductive drum 1012 is scattered and drifts to the downstream side of these rotation directions. Accordingly, an exhaust duct 1060 whose suction opening is above the vicinity of the position where the developing roller 1014a opposes the photoconductive drum 1012 (developing position) is arranged on the downstream side of the rotation directions of the developing roller 1014a and the photoconductive drum 1012. It should be noted that toner is supplied to the developing roller 1014a of the developing cartridge 1014 by pressing a supply roller 1014b rotating within the toner containing space of the developing cartridge 1014 against the developing roller 1014a.

As shown in FIG. 17, the exhaust duct 1060 includes a suction opening 1061, an exhaust path 1062, and an exhaust opening 1063. The suction opening 1061 is arranged above the vicinity of the developing position where the developing roller 1014a of the developing cartridge 1014 faces the photoconductive drum 1012 (the vicinity of the developing position on the inward side, with respect to the apparatus main unit, of the developing rotary unit 1015). The exhaust path 1062 describes an exhaust flow channel from the suction opening 1061, going around and covering the upper side of the developing rotary unit 1015 toward the external cover 1100 on the side of the side wall, and then descending along the external cover 1100. A suction fan 1063a sucking air inside the exhaust path 1062 is arranged in the exhaust opening 1063, which is disposed near the bottom of the developing rotary unit 1015 adjacent to the external cover 1100 on the side of the side wall. A filter 1064, which adsorbs and removes toner that has become intermingled in the suction air, is arranged in the exhaust path 1062 of the exhaust duct 1060, positioned above the developing rotary unit 1015. Thus, a

design is achieved with which no toner is included in the exhaust air discharged from the exhaust opening 1063, polluting the surroundings.

Moreover, as shown in FIG. 21, the suction opening 1061, which is so large that it covers the entire main scanning direction (axial length) of the exhaust duct 1060, sucks in the air above the vicinity of the developing position where the developing roller 1014a of the developing cartridge 1014 faces the photoconductive drum 1012. The air is ejected and exhausted from the exhaust opening 1063, which has a small opening, in which the suction fan 1063a is arranged. The exhaust path 1062 between the suction opening 1061 and the exhaust opening 1063 is defined by a duct plate 1065 that is shaped such that it is constricted from the suction opening 1061 having an opening width of approximately the entire width of the photoconductive drum 1012 toward the exhaust opening 1063 having an opening width of approximately its end portion.

A wall surface 1065a of the duct plate 1065 is arranged next to the main unit-side antenna 1051 and the send-receive circuit 1052 at a position of the exhaust duct 1060 that is closest to the external cover 1100, like the main unit-side antenna 1051 and the send-receive circuit 1052 on the apparatus main unit side. A plurality of drainage openings 1066 through which air within the apparatus main unit around the wall surface 1065a can flow into the exhaust path 1062, are provided in the wall surface 1065a. That is to say, when the suction fan 1063a is driven and the air inside the exhaust path 1062 is sucked and exhausted, then the exhaust duct 1060 also drains the air in the vicinity of the communication position of the memory tag 1041 of the developing cartridge 1014 and the main unit-side antenna 1051 (this includes also the vicinity of the send-receive circuit 1052) through the drainage openings 1066, thereby resulting in a ventilation means that forcibly blows air onto the memory tag 1041 and the like.

Thus, a layout is achieved in which the memory tag 1041 of the developing cartridge 1014 and the send-receive circuit 1052 are positioned at a communication position (region) that is closest to the external cover 1100, so that they are positioned in an environment that is closest to the external temperature and it can be avoided that their internal elements are affected by heat, leading to a drop in the processing speed or the like. In addition to this, as the exhaust duct 1060 (suction fan 1063a) provides suction in the vicinity of the region above the developing position where the developing roller 1014a of the developing cartridge 1014 faces the photoconductive drum 1012, the surrounding air flows from the drainage openings 1066 into the exhaust path 1062 of the exhaust duct 1060 during operation of the apparatus main unit, so that air whose temperature is close to that of the outside is always blown against the memory tag 1041 of the developing cartridge 1014 and the send-receive circuit 1052 (i.e. they are exposed to such air), thereby cooling them. Consequently, the memory tag 1041 of the developing cartridge 1014 and the send-receive circuit 1052 on the apparatus main unit side can carry out various processes, such as a communication operation or the reading and rewriting of stored information, without the occurrence of errors, simultaneously and with high efficiency, in an environment in which operation is possible without heating up of their internal elements.

Thus, in this embodiment, the memory tag 1041 on the outer surface of the developing cartridge 1014 in the communication position and the send-receive circuit 1052 on the apparatus main unit side are furthest removed from the pair of fixing rollers 1018 and the laser beam scanning device 1011, in an environment in which they are closest to the external cover 1100 of the apparatus main unit, and the suction (flow)

of air in the exhaust duct **1060** is utilized to blow air onto their surroundings, so that it can be avoided that the temperature rises unnecessarily, and communication in a noncontacting manner and reading/rewriting of stored information can be accomplished with high efficiency and without errors, without being subjected to the thermal influence due to the generation of heat externally (inside the apparatus main unit) or internally (within their internal elements). Consequently, the processes of rewriting or reading the various kinds of information in the memory tags **1041** of each of the developing cartridges **1014** can be carried out accurately and speedily without impeding the image formation process, and the information that is necessary for the drive control of the various components of the apparatus can be made accessible in a smooth manner.

As a first alternative form of this embodiment, it is also possible to arrange vent holes **1071** at the top and the bottom of the external cover **1100**, such that air from outside the apparatus can flow into and pass through the apparatus main unit between the memory tag **1041** of the developing cartridge **1014** at the communication position adjacent to (closest to) the external cover **1100** and the main unit-side antenna **1051** and the send-receive circuit **1052** on the apparatus main unit side, even if no exhaust duct **1060** is provided as in the present embodiment, and it is also possible to provide guide plates **1072** so that the in-flowing external air flows between the memory tag **1041** of the developing cartridge **1014** and the main unit-side antenna **1051** on the apparatus main unit side, as shown FIG. 22. In this case, air is not forcibly blown as in the present embodiment, but it is possible to let external air flow in without being impeded by the external cover **1100**, so that as a result, the memory tag **1041** and the like can be cooled. Needless to say, it is also possible to apply the vent holes **1071** and the guide plates **1072** to the present embodiment to achieve more effective cooling.

As a second alternative form of this embodiment, the present invention can also be applied to cases in which, instead of an antenna for communication in a noncontacting manner as in the present embodiment, a connector **1076** provided with electrode terminals **1075** is connected with the send-receive circuit **1052** on the apparatus main unit side, and a memory tag **1077** with exposed electrode terminals not shown in the drawings is placed on the side of the developing cartridge **1014**, as shown in FIG. 23, so that during communication, the connector **1076** approaches the memory tag **1077** and the electrode terminals **1075** are pressed against each other, thereby establishing a connection allowing communication by contact. In this case, as in the above embodiment, the memory tag **1077** on the outer surface of the developing cartridge **1014** in the communication position and the send-receive circuit **1052** on the apparatus main unit side can be cooled more effectively by utilizing the suction (flow) of air from the exhaust duct **1060** to blow air onto their surroundings, in an environment, in which they are closest to the external cover **1100** of the apparatus main unit and removed from heat-generating members, such as the pair of fixing rollers **1018**.

With this embodiment, during communication, the storage element on the outer surface of the developing cartridge is positioned at a position where it is closest to the external cover of the apparatus main unit, so that the thermal influence of devices that are heat-generating members within the apparatus main unit is small and it is possible to perform the communication processes of reading and writing stored information. Consequently, it is possible to avoid errors occurring during the reading and writing of information stored in the storage element, or that the performance of the communica-

tion processing of this stored information drops. As a result, by accessing the storage element of each developing cartridge accurately and speedily, it is possible to smoothly utilize the information stored in the storage elements for the drive control of the image processing or the like.

The preceding was an explanation of an embodiment of the present invention, but the present invention is not limited to this embodiment, and needless to say, the present invention can be embodied through various different forms within the technical scope of the invention. For example, in the present embodiment, an image forming apparatus is explained, in which the developing cartridges are stored in a developing rotary unit, but there is not limitation to this, and for example, it is also possible to apply the present invention to an image forming apparatus with a configuration, in which the developing cartridges are lined up side by side, or one in which the developing cartridges are disposed around the photoconductive drum. Furthermore, in the present embodiment, an example of developing cartridges is explained, in which the developing roller is integrally attached to a container containing the toner, but there is no limitation to this, and it is also possible to devise a developing cartridge in which a developing device, such as the developing roller, and a toner-containing container (toner cartridge) are fabricated as separate members and mounted separately in the apparatus main unit.

Overview of Image Forming Apparatus of Third Embodiment

The following is an explanation of a third embodiment of the present invention, with reference to the drawings. FIGS. 24 to 28 are diagrams showing an embodiment of an image forming apparatus according to a third embodiment of the present invention.

In FIG. 24 and FIG. 25, the image forming apparatus is a printer that is used by connecting it to an external device such as a personal computer PC that creates and outputs images of text or the like. This image forming apparatus includes an image recording device **2010** that records and forms images on one side or both sides of recording paper (recording medium) through electrophotography by reading in image data of text or the like to be image-formed, a paper carry device **2020** that carries a plurality of stacked recording papers to the image recording device **2010** and carries the recording paper on which an image has been recorded and formed out of the apparatus, stacking the recording paper, and a control unit **2030** that is connected to a personal computer PC and makes print-outs by forming images on the recording paper through comprehensive control of the overall apparatus including the image recording device **2010** and the paper carry device **2020** in accordance with the image data that has been received.

Simply speaking, the image recording device **2010** includes, as shown in FIG. 24, a laser beam scanning device **2011** scanning a laser beam **L1** based on image data, a photoconductive drum (bearing member) **2012** on the surface of which an electrostatic latent image is exposed and formed based on image data that is irradiated and scanned with the laser beam **L1** from the laser beam scanning device **2011**, a charge device **2013** charging the outer circumferential surface of the photoconductive drum **2012** such that an electrostatic latent image can be formed by irradiating the laser beam **L1**, a developing cartridge **2014** (shown only at one place) for each of the colors, which contains yellow (Y), cyan (C), magenta (M) or black (K) toner and performs toner development of the electrostatic latent image on the photoconductive drum **2012**, a developing rotary unit **2015** holding the devel-

oping cartridges 2014 in preset spaces 2015a for each color and rotating them around a rotation shaft 2015b, an intermediate image transfer belt (intermediate image transfer medium) 2016, which can receive the toner image developed on the photoconductive drum 2012 so that a toner image (monochrome image or color image) is formed on it that can be transferred and recorded on recording paper, an image transfer roller 2017 transferring the toner image carried on the intermediate image transfer belt 2016 by applying a contact pressure (nip) such that the recording paper carried up to it is sandwiched between the image transfer roller 2017 and the intermediate image transfer belt 2016, and carrying the recording paper downstream while clamping the recording paper, a pair of fixing rollers 2018 fixing the toner image by applying heat and contact pressure to the recording paper onto which the toner image has been transferred and which has been carried up to them, and clamping and carrying the recording paper further downstream, and a waste toner tank 2019 collecting and accumulating toner that has remained on the photoconductive drum 2012 with a blade 2019a.

Thus, in the image recording device 2010, the developing cartridge 2014 inside the developing rotary unit 2015 that has been switched in accordance with the image data develops with toner the electrostatic latent image based on the image data formed on the surface of the photoconductive drum 2012 with the laser beam scanning device 2011. And after that, the toner image on the photoconductive drum 2012 is transferred and recorded via the intermediate image transfer belt 2016 onto recording paper that has been carried with the paper carry device 2020, and then fixed by applying heat and pressure with the pair of fixing rollers 2018, thus accomplishing image formation. It should be noted that the intermediate image transfer belt 2016, the image transfer roller 2017 and the pair of fixing rollers 2018 of this image recording device also have the function of carrying the recording paper, so that they also constitute a part of the paper carry device 2020 explained below. Also the unit of the intermediate image transfer belt 2016 is provided with a waste toner tank in which the toner remaining on the belt 2016 is collected with a blade and stored.

Simply speaking, the paper carry device 2020 includes, as shown in FIG. 24, a paper cassette 2021, which is removably set in a lower section of the apparatus main unit and in which a plurality of sheets of recording paper are stacked, a pick-up roller 2022, which picks up the uppermost recording paper by rotating while being pressed against the stack of recording paper that has been elevated with an elevating plate 2021a at the bottom surface of the paper cassette 2021, thereby feeding the recording paper to a carry path f, a pair of relay carry rollers 2023a and 2023b, which receive the recording paper that is fed to them by the pick-up roller 2022 and clamp and carry the recording paper to the carry path f further downstream, a pair of registration rollers 2024, which receive the recording paper in the carry path f that is carried by the pair of relay carry rollers 2023a and 2023b and clamp and carry the recording paper to an image recording formation position given by the intermediate image transfer belt 2016 and the image transfer roller 2017 of the image recording device 2010, and a pair of paper discharge rollers 2025a and 2025b, which receive the recording paper on one side of which a fixed image has been formed by carrying the recording paper along the carry path f from the pair of registration rollers 2024, between the intermediate image transfer belt 2016 and the image transfer roller 2017 and between the pair of fixing rollers 2018, and which carries and discharges and stacks the recording paper on a paper discharge table 2029 on top of the apparatus main unit.

Thus, after the recording paper that has been picked up from the paper cassette 2021 with the pick-up roller 2022 has been passed on via the pair of relay carry rollers 2023a and 2023b to the pair of registration rollers 2024, the paper carry device 2020 supplies the recording paper to the image recording formation position at which the recording paper is pressed against by the intermediate image transfer belt 2016 and the image transfer roller 2017 such that the pair of registration rollers 2024 is synchronized with the operation of the image recording device 2010. The recording paper, on which the toner image on the intermediate image transfer belt 2016 has been transferred and recorded, and the image based on the image data has been fixed (recording formation) with the pair of fixing rollers 2018, is received by the pair of paper discharge rollers 2025a and 2025b and is carried and ejected and stacked on the paper discharge table 2029.

It should be noted that this paper carry device 2020 includes a reverse carry path r and a pair of intermediate carry rollers 2027 disposed on this path r for turning over recording paper on one side of which an image has been formed and feeding it to the carry path f on the upstream side of the pair of registration rollers 2024. The recording paper, which has been fed into the reverse carry path r by inverting the rotation of the pair of paper discharge rollers 2025a and 2025b is received by the pair of intermediate carry rollers 2027 and passed on to the pair of registration rollers 2024, so that image formation on both sides of the recording paper is possible. Moreover, the paper carry device 2020 includes a manual feed path m and a pair of manual feed rollers 2028 disposed on this path m for manually feeding recording paper into the carry path f on the upstream side of the pair of registration rollers 2024. Image formation on one side or both sides of the recording paper is possible by receiving the recording paper inserted into this manual feed path m with the pair of manual feed rollers 2028 and passing it to the pair of registration rollers 2024.

As shown in FIG. 25, the control unit 2030 includes a controller section 2031 and an engine controller 2032 implemented on a circuit board mounted inside the apparatus main unit. These perform various kinds of data process control and drive control of the various components of the apparatus in accordance with a program that is provided in advance.

Simply speaking, the controller section 2031 exchanges various kinds of information, such as print commands, with a printer driver of a personal computer PC, with a CPU not shown in the drawings successively executing various processes in accordance with a processing program stored in a memory, receives image data, such as text, to be formed as an image (printed) on the recording paper, and temporarily stores the image data in a memory not shown in the drawings. Since the image data (image information signal) received from the personal computer PC is so-called RGB data of red (R), green (G) and blue (B), the controller section 2031 reads the data from the memory and passes it to the engine controller 2032 while converting this data into so-called YMCK image data of yellow (Y), magenta (M), cyan (C) and black (K) that can be printed.

With the CPU 2033 following the control program stored in the ROM 2034, the engine controller 2032 receives the image data page by page, for example, from the controller section 2031 and temporarily stores it in a main unit-side memory 2035, and an image based on this image data is formed on the recording paper by exchanging various kinds of information with the image recording device 2010 and the paper carry device 2020 while using a RAM 2036 as a working area. Moreover, when the CPU 2033 performs the image formation control at this time, it lets each component of the apparatus

operate optimally by measuring the various processing times with an internal timer function (time measurement means) 2033a.

Thus, when the control unit 2030 receives image data from the personal computer PC or the like, the controller section 2031 outputs image data, which it has converted from RGB data to YMCK data, to the engine controller 2032, while temporarily storing the image data. The CPU 2033 of the engine controller 2032 comprehensively controls the image recording device 2010 and the paper carry device 2020 based on the image data from the controller section 2031 stored in units of pages in the main unit memory 2035. In accordance with this control, the electrostatic latent image formed on the photoconductive drum 2012 based on the image data is developed with toner by the developing cartridge 2014, and this toner image is transferred to and fixed on one or both sides of recording paper that has been carried from the paper cassette 2021 to form an image, and the recording paper is carried to and stacked on the paper discharge table 2029.

It should be noted that in FIG. 25, an I/O interface 2037 is connected between the image recording device 2010, the paper carry device 2020 and the controller section 2031 on the one hand and the engine controller 2032 on the other hand, such that various kinds of information can be exchanged. A D/A converter 2038 and an A/D converter 2039 convert digital signals (D) into analog signals (A) and convert analog signals into digital signals, such that the various kinds of information that the engine controller 2032 exchanges with the image recording device 2010, the paper carry device 2020 and the controller section 2031 can be processed by these.

The developing cartridges 2014 of the image recording device 2010 are provided with a similar external shape, such that they can be accommodated in a plurality of storage positions that are partitioned by partitioning frames 2015c that rotate around the rotation shaft 2015b of the developing rotary unit 2015. Based on the print commands included in the image data from the personal computer PC, the CPU (controller) 2033 of the engine controller 2032 lets the developing rotary unit 2015 rotate around the rotation shaft 2015b to switch the developing cartridge 2014 facing the photoconductive drum 2012 and develop the toner image formed by transferring/fixing toner on one side or both sides of the recording paper.

For example, by storing in the developing rotary unit 2015 developing cartridges 2014 containing toner of the colors yellow (Y), cyan (C), magenta (M) and black (K) and switching the color of the toner for developing the electrostatic latent image on the photosensitive drum 2012, the image recording device 2010 can superimpose or select toner of various colors and print color images or monochrome images, based on the received image data.

Moreover, the image recording device 2010 can also perform image formation when toner of the same color is contained in all developing cartridges 2014 and those developing cartridges 2014 are mounted in the developing rotary unit 2015. For example, by mounting four developing cartridges 2014 containing toner of the same color black (K), it is possible to use the apparatus as a special purpose apparatus that successively switches the developing cartridges 2014 developing the electrostatic latent image on the photoconductive drum 2012 and continuously prints and forms monochrome images.

A so-called memory tag 2041 that is overall very compact and thin is adhered to a predetermined outer surface of each of the developing cartridges 2014 by making one side of it adhesive. When the memory tag 2041 is moved to a rotation position (communication position) facing a main unit-side

antenna 2051 on the main unit side of the apparatus shown in FIG. 24, then it is arranged at a position along an external cover 100 of the apparatus main unit, or in other words, it is placed (adhered) on the outer surface of the developing cartridge 2014 in an upright orientation and at a position where it is closest to this external cover 100 and facing it. This memory tag 2041 is designed to store and hold relevant information and to pass the relevant information to the CPU 2033 of the engine controller 2032 by communicating in a noncontacting manner with a send-receive circuit 2052 on the apparatus main unit side via the main unit-side antenna 2051 to exchange various kinds of information. Here, the main unit-side antenna 2051, which is placed in a downward-facing orientation (an orientation in which no dust and dirt accumulates on it) on the apparatus main unit side, is fabricated in substantially the same manner as a later-described developing-side antenna 2043. The main unit-side antenna 2051 is placed within a distance of, for example, 10 mm of the memory tag 2041, so as to be able to communicate in a noncontacting manner with the memory tag 2041. The main unit-side antenna 2051 is connected to a circuit board constituting the send-receive circuit 2052 and performing communication in a noncontacting manner with the memory tag 2041. This send-receive circuit 2052 is connected via the I/O interface 2037 to the CPU 2033 of the engine controller 2032 on the apparatus main unit side.

More specifically, as shown in FIG. 26(a), in the memory tag 2041 on the side of the developing cartridge 2014, a non-contact IC chip 2042 and the developing-side antenna 2043 are mounted on a plastic film and covered by a transparent cover sheet. The non-contact IC chip 2042 stores and holds various kinds of information based on commands from the send-receive circuit 2052 via the main unit-side antenna 2051 and reads relevant information from these various kinds of information, passing on the relevant information to the send-receive circuit 2052. The developing-side antenna 2043 is made by connecting in parallel the non-contact IC chip 2042 and a resonance capacitor 2043a that is formed by etching a metal film, and arranging a planar coil next to these, the planar coil going several times around the non-contact IC chip 2042 and the resonance capacitor 2043a. Thus, by receiving (absorbing) with the developing-side antenna 2043 a high-frequency magnetic field induced via the main unit-side antenna 2051 by high-frequency signals generated with the send-receive circuit 2052 on the apparatus main unit side, it is possible to access the memory tag 2041 quickly and perform an input into the non-contact IC chip 2042, without carrying out an operation of moving a connector and directly connecting it.

As shown in FIG. 26(b), the non-contact IC chip 2042 of the memory tag 2041 includes a rectifier 2044 serving as a DC power source that rectifies the high-frequency magnetic field (high-frequency signals) from the send-receive circuit 2052 on the apparatus main unit side received via the developing-side antenna 2043 and drives the various circuits within the chip, a signal analysis section RF (Radio Frequency) 2045, which analyzes the high-frequency signals of the received high-frequency magnetic field received via the developing-side antenna 2043 and generates a high-frequency magnetic field that can be absorbed by the main unit-side antenna 2051 by generating a high-frequency signal based on the various kinds of signals to be passed on to the send-receive circuit 2052 on the apparatus main unit side and inputting this high-frequency signal to the developing-side antenna 2043, a non-volatile memory cell 2046, such as a NAND flash-ROM or the like, that can store and hold information written into it and from which this stored information can be read out from the

outside, and a controller 2047, which rewrites the information stored in the memory cell 2046 by exchanging various kinds of signals with the send-receive circuit 2052 on the side of the apparatus main unit via the signal analysis section RF 2045 and passes the stored information that has been read out to the send-receive circuit 2052, while being driven by the DC power source of the interposed rectifier 2044. That is to say, the memory cell 2046 constitutes a storage element, the developing-side antenna 2043 and the main unit-side antenna 2051 constitute a connection link that can be connected to enable communication in a noncontacting manner, the non-contact IC chip 2042 incorporating the memory cell 2046 and the developing-side antenna 2043 constitute a communication means (communication section) for communication in a noncontacting manner on the side of the developing cartridge 2014, whereas the main unit-side antenna 2051 and the send-receive circuit 2052 constitute a communication means (communication section) on the apparatus main unit side.

Here, stored and held inside the memory cell 2046 of the non-contact IC chip 2042 are unique ID information, such as a serial number for each memory tag 2041, manufacturing information, such as the date when the developing cartridge 2014 was manufactured or the manufacturing number, destination information specifying the destination of the developing cartridge 2014, model information specifying models to which the developing cartridge 2014 can be mounted, toner information, such as information on the color and the remaining amount of toner contained in the developing cartridge 2014, and various kinds of relevant information, such as the number of recycles or the number of times the developing cartridge 2014 has been mounted and dismounted. Thus, the engine controller 2032 of the control unit 2030 can perform an optimal image formation control, by suitably ascertaining various kinds of information that the CPU 2033 has stored and held in the main unit-side memory 2035, such as the presence and the position of the developing cartridge 2014 in the storage position of the developing rotary unit 2015, or information about the color of the toner of the developing cartridge 2014. Moreover, if an error occurs, the various kinds of information can be useful in finding the cause of the error by displaying/outputting the information to an operation port.

Moreover, through synchronized rotation of the developing roller 2014a facing the surface of the photoconductive drum 2012 via a gap, the developing cartridge 2014 performs toner development by transferring toner and letting it adhere to the electrostatic latent image formed on that surface. The photoconductive drum 2012 rotates clockwise in FIG. 24, whereas the developing roller 2014a rotates counterclockwise in FIG. 24, so that a small fraction of the toner that is about to be transferred from the developing roller 2014a to the photoconductive drum 2012 is scattered and drifts to the downstream side of these rotation directions. Accordingly, an exhaust duct 2060 whose suction opening is above the vicinity of the position where the developing roller 2014a opposes the photoconductive drum 2012 (developing position) is arranged on the downstream side of the rotation directions of the developing roller 2014a and the photoconductive drum 2012. It should be noted that toner is supplied to the developing roller 2014a of the developing cartridge 2014 by pressing a supply roller 2014b rotating within the toner containing space of the developing cartridge 2014 against the developing roller 2014a.

As shown in FIG. 24, the exhaust duct 2060 includes a suction opening 2061, an exhaust path 2062 and an exhaust opening 2063. The suction opening 2061 is arranged above the vicinity of the developing position where the developing roller 2014a of the developing cartridge 2014 faces the photoconductive drum 2012 (the vicinity of the developing position on the inward side, with respect to the apparatus main unit, of the developing rotary unit 2015). The exhaust path 2062 describes an exhaust flow channel from the suction opening 2061, going around and covering the upper side of the developing rotary unit 2015 toward the external cover 1100 on the side of the side wall, and then descending along the external cover 1100. A suction fan (not shown in the drawings) sucking air inside the exhaust path 2062 is arranged in the exhaust opening 2063, which is disposed near the bottom of the developing rotary unit 2015 adjacent to the external cover 1100 on the side of the side wall. A filter 2064, which adsorbs and removes toner that has become intermingled in the suction air, is arranged in the exhaust path 2062 of the exhaust duct 2060, positioned above the developing rotary unit 2015. Thus, a design is achieved with which no toner is included in the exhaust air discharged from the exhaust opening 2063, polluting the surroundings.

Moreover, as shown in FIG. 27, the suction opening 2061 of the exhaust duct 2060 is formed so that it is shorter than the width W1 of the developing position in the main scanning direction (axial direction) where the developing roller 2014a of the developing cartridge 2014 faces the photoconductive drum 2012, for example to a width W2 of about 1/4 thereof, and is designed to provide suction above the vicinity of this developing position. In the exhaust duct 2060, a suction fan is driven such that its suction force reaches the entire length in the main scanning direction above the vicinity of the developing position from the suction opening 2061.

At this time, the suction opening 2061 of the exhaust duct 2060 approaches both the photoconductive drum 2012 and the developing roller 2014a (to an extent that it does not contact the developing roller 2014a during the rotation of the developing cartridge 2014) and provides suction above the developing position where they face each other, so that it is possible to effectively draw in air over the entire length above the vicinity of the developing position where the photoconductive drum 2012 faces the developing roller 2014a, without drawing in a large amount of air from locations outside the developing position (for example from the open space removed from the end in axial direction of the photoconductive drum 2012 or the developing roller 2014a), and toner t drifting above the vicinity of the developing position can be collected on the side of the suction opening 2061 and sucked in, as shown in FIG. 28.

Thus, the toner t drifting in the vicinity of the developing position where the photoconductive drum 2012 faces the developing roller 2014a of the developing cartridge 2014 is collected near the suction opening 2061 of the exhaust duct 2060, which is arranged at the center in the main scanning direction of these and is effectively sucked in, so that even if the developing cartridge 2014 is rotated before the toner is completely sucked away, hardly any toner will adhere to its outer surface, and even if some toner adheres thereto, toner can be kept from adhering to the entire outer surface of the developing cartridge 2014 by simply moving along a narrow region of the outer surface near the middle of the developing cartridge 2014.

On the other hand, when the developing rotary unit 2015 rotates, the memory tag 2041, which is placed on the outer surface of the developing cartridge 2014, is placed on the outer surface of the developing cartridge 2014 at a location that is further to the right in FIG. 27 than the range that faces the suction opening 2061 of the exhaust duct 2060 while moving relative to it (that is, the range passing near the suction opening 2061), so that also the main unit-side antenna 2051 on the apparatus main unit side is arranged at a commu-

nication position that is set at a position to the rearward side with respect to the paper plane of FIG. 24, so that it faces the memory tag 2041 (the developing-side antenna 2043).

Thus, the reading and rewriting of information stored in the memory cell 2046 can be accomplished with high reliability and accuracy, without the memory tag 2041 on the outer surface of the developing cartridge 2014 coming close to the suction opening 2061 of the exhaust duct 2060, without its surface (the developing-side antenna 2043) being polluted by toner t drawn in from this suction opening 2061, and without communication faults (connection faults) due to a decrease in the sensitivity of the signals exchanged with the main unit-side antenna 2051 while performing communication in a noncontacting manner. As a result, various kinds of processes, such as communication in a noncontacting manner, can be accomplished quickly between the memory tag 2041 and the send-receive circuit 2052, and it can be avoided that the toner t accumulating on the surface of the memory tag 2041 adheres and undergoes a reaction or the like.

Thus, in this embodiment, it can be avoided that toner t drifting near the suction opening 2061 of the exhaust duct 2060 contacts the surface of the memory tag 2041 (the developing-side antenna 2043 or the memory cell 2046) on the outer surface of the developing cartridge 2014, and unnecessarily adheres or accumulates thereon, and communication in a noncontacting manner and the reading and rewriting of stored information can be accomplished with high efficiency and without errors, without adversely affecting that surface or the internal elements and without connection faults (communication faults in the communication in a noncontacting manner) between the developing-side antenna 2043 and the main unit-side antenna 2051. Consequently, the processes of rewriting or reading the various kinds of information in the memory tags 2041 of each of the developing cartridges 2014 can be carried out accurately and speedily, and the information that is necessary for the drive control of the various components of the apparatus can be made accessible in a smooth manner.

As an alternative form of this embodiment, the present invention can also be applied to cases in which, instead of an antenna for communication in a noncontacting manner as in the present embodiment, a connector 2072 provided with electrode terminals 2071 is connected with the send-receive circuit 2052 on the apparatus main unit side, and a memory tag 2073 with exposed electrode terminals not shown in the drawings is placed on the side of the developing cartridge 2014, as shown in FIG. 29, so that during communication, the connector 2072 approaches the memory tag 2073 and the electrode terminals 2071 are pressed against each other, thereby establishing a connection allowing communication by contact. In this case, as in the above embodiment, it can be avoided that dust or dirt unnecessarily adheres or accumulates on the surface of the memory tag 2073 (electrode terminal) on the outer surface of the developing cartridge 2014 in the communication position, and the connector 2072 can be brought with high reliability into conductive contact with the memory tag 2073 of each of the developing cartridges 2014, so that the processes of rewriting and reading the various kinds of information in the memory cell can be carried out accurately and speedily.

Moreover, in the above embodiment, an example was explained, in which the suction opening 2061 of the exhaust duct 2060 is formed narrowly, but there is no limitation to this. For example, also when the suction opening has a width of approximately the entire length in axial direction of the photoconductive drum 2012, it is possible to place the memory

tag such that it is positioned further outside than the suction opening on the outer surface of the developing cartridge.

With the present embodiment, even when toner drifts in the vicinity of the suction opening of the duct, the storage element on the outer surface of the developing cartridge and the connection section on the apparatus main unit side are not moved through a region where this toner drifts, and it can be avoided that this drifting toner accumulates and pollutes them, thus becoming a cause for connection faults. Consequently, it is possible to establish communication by which the information stored in the storage element can be exchanged accurately, without affecting the storage element and without the occurrence of connection faults between the developing cartridge side and the apparatus main unit side. As a result, it is possible to read out or rewrite the information stored in the storage element on the outer surface of the developing cartridge with high reliability, and to accurately access the storage element of each developing cartridge to smoothly utilize the information stored in the storage element for the drive control of the image processing or the like.

The preceding was an explanation of an embodiment of the present invention, but the present invention is not limited to this embodiment, and needless to say, the present invention can be embodied through various forms within the technical scope of the invention.

Overview of Image Forming Apparatus of Fourth Embodiment

The following is an explanation of a fourth embodiment of the present invention, with reference to the drawings. FIGS. 31 to 36 are diagrams showing an embodiment of an image forming apparatus according to the present invention.

In FIG. 31 and FIG. 32, the image forming apparatus is a printer that is used by connecting it to an external device such as a personal computer PC that creates and outputs images of text or the like. This image forming apparatus includes an image recording device 3010 that records and forms images on one side or both sides of recording paper (recording medium) through electrophotography by reading in image data of text or the like to be image-formed, a paper carry device 3020 that carries a plurality of stacked recording papers to the image recording device 3010 and carries the recording paper on which an image has been recorded and formed out of the apparatus, stacking the recording paper, and a control unit 3030 that is connected to a personal computer PC and makes print-outs by forming images on the recording paper through comprehensive control of the overall apparatus including the image recording device 3010 and the paper carry device 3020 in accordance with the image data that has been received and the like.

Simply speaking, the image recording device 3010 includes, as shown in FIG. 31, a laser beam scanning device 3011 scanning a laser beam L1 based on image data, a photoconductive drum (bearing member) 3012 on the surface of which an electrostatic latent image is exposed and formed based on image data that is irradiated and scanned with the laser beam L1 from the laser beam scanning device 3011, a charge device 3013 charging the outer circumferential surface of the photoconductive drum 3012 such that an electrostatic latent image can be formed by irradiating the laser beam L1, a developing cartridge 3014 (shown only at one place) for each of the colors, which contains yellow (Y), cyan (C), magenta (M) or black (K) toner and selectively lets the contained toner adhere to perform toner development of the electrostatic latent image on the surface of the photoconductive drum 3012 by rotating, in synchronization, developing rollers

3014a facing the surface of the photoconductive drum **3012** across a gap, a developing rotary unit **3015** holding the developing cartridges **3014** in preset spaces **3015a** for each color and rotating them around a rotation shaft **3015b**, an intermediate image transfer belt (intermediate image transfer medium) **3016**, which can receive the toner image developed on the photoconductive drum **3012** so that a toner image (monochrome image or color image) is formed on it that can be transferred and recorded on recording paper, an image transfer roller **3017** transferring the toner image carried on the intermediate image transfer belt **3016** by applying a contact pressure (nip) such that the recording paper carried up to it is sandwiched between the image transfer roller **3017** and the intermediate image transfer belt **3016**, and carrying the recording paper downstream while clamping the recording paper, a pair of fixing rollers **3018** fixing the toner image by applying heat and contact pressure to the recording paper onto which the toner image has been transferred and which has been carried up to them, and clamping and carrying the recording paper further downstream, and a waste toner tank **3019** collecting and accumulating toner that has remained on the photoconductive drum **3012** with a blade **3019a**. It should be noted that toner is supplied to the developing roller **3014a** of the developing cartridge **3014** by pressing and rotating a supply roller **3014b** rotating within the toner containing space of the developing cartridge **3014** against the developing roller **3014a**. Also the unit of the intermediate image transfer belt **3016** is provided with a waste toner tank in which the toner remaining on the belt **3016** is collected with a blade and stored.

Thus, in the image recording device **3010**, the developing cartridge **3014** inside the developing rotary unit **3015** that has been switched in accordance with the image data develops with toner the electrostatic latent image based on the image data formed on the surface of the photoconductive drum **3012** with the laser beam scanning device **3011**. And after that, the toner image on the photoconductive drum **3012** is transferred and recorded via the intermediate image transfer belt **3016** onto recording paper that has been carried with the paper carry device **3020**, and then fixed by applying heat and pressure with the pair of fixing rollers **3018**, thus accomplishing image formation.

Here, with this developing cartridge **3014**, when the developing roller **3014a** that rotates while facing the photoconductive drum **3012** across the gap transfers and adheres contained toner to the surface of the photoconductive drum **3012**, a small fraction of the toner is scattered and drifts to the downstream side in the rotation direction, so that an exhaust duct **3060** sucks in air with a suction fan not shown in the drawings from a suction opening **3061** above the vicinity of the position where the developing roller **3014a** opposes the photoconductive drum **3012**, and exhausts the air via an exhaust path **3062** from an exhaust opening **3063**. The toner included in the air that is sucked in is adsorbed and removed by a filter **3064** arranged midway in the exhaust path **3062**, thereby preventing the outside of the apparatus from being polluted.

Simply speaking, the paper carry device **3020** includes, as shown in FIG. 31, a paper cassette **3021**, which is removably set in a lower section of the apparatus main unit and in which a plurality of sheets of recording paper are stacked, a pick-up roller **3022**, which picks up the uppermost recording paper by rotating while being pressed against the stack of recording paper that has been elevated with an elevating plate **3021a** at the bottom surface of the paper cassette **3021**, thereby feeding the recording paper to a carry path **f**, a pair of relay carry rollers **3023a** and **3023b**, which receive the recording paper that is fed to them by the pick-up roller **3022** and clamp and

carry the recording paper to the carry path **f** further downstream, a pair of registration rollers **3024**, which receive the recording paper in the carry path **f** that is carried by the pair of relay carry rollers **3023a** and **3023b** and clamp and carry the recording paper to an image recording formation position given by the intermediate image transfer belt **3016** and the image transfer roller **3017** of the image recording device **3010**, and a pair of paper discharge rollers **3025a** and **3025b**, which receive the recording paper on one side of which a fixed image has been formed by carrying the recording paper along the carry path **f** from the pair of registration rollers **3024**, between the intermediate image transfer belt **3016** and the image transfer roller **3017** and between the pair of fixing rollers **3018**, and which carries and discharges and stacks the recording paper on a paper discharge table **3029** on top of the apparatus main unit. It should be noted that the intermediate image transfer belt **3016**, the image transfer roller **3017** and the pair of fixing rollers **3018** of this image recording device also have the function of carrying the recording paper, so that they also constitute a part of the paper carry device **3020**.

Thus, after the recording paper that has been picked up from the paper cassette **3021** with the pick-up roller **3022** has been passed on via the pair of relay carry rollers **3023a** and **3023b** to the pair of registration rollers **3024**, the paper carry device **3020** supplies the recording paper to the image recording formation position at which the recording paper is pressed against by the intermediate image transfer belt **3016** and the image transfer roller **3017** such that the pair of registration rollers **3024** is synchronized with the operation of the image recording device **3010**. The recording paper, on which the toner image on the intermediate image transfer belt **3016** has been transferred and recorded, and the image based on the image data has been fixed (recording formation) with the pair of fixing rollers **3018**, is received by the pair of paper discharge rollers **3025a** and **3025b**, and is carried and ejected and stacked on the paper discharge table **3029**.

Here, this paper carry device **3020** includes a reverse carry path **r** and a pair of intermediate carry rollers **3027** disposed on this path **r** for turning over recording paper on one side of which an image has been formed and feeding it to the carry path **f** on the upstream side of the pair of registration rollers **3024**. The recording paper, which has been fed into the reverse carry path **r** by inverting the rotation of the pair of paper discharge rollers **3025a** and **3025b**, is received by the pair of intermediate carry rollers **3027** and passed on to the pair of registration rollers **3024**, so that image formation on both sides of the recording paper is possible. Moreover, the paper carry device **3020** includes a manual feed path **m** and a pair of manual feed rollers **3028** disposed on this path **m** for manually feeding recording paper into the carry path **f** on the upstream side of the pair of registration rollers **3024**. Image formation on one side or both sides of the recording paper is possible by receiving the recording paper inserted into this manual feed path **m** with the pair of manual feed rollers **3028** and passing it to the pair of registration rollers **3024**.

As shown in FIG. 32, the control unit **3030** includes a controller section **3031** and an engine controller **3032** implemented on a circuit board mounted inside the apparatus main unit. These perform various kinds of data process control and drive control of the various components of the apparatus in accordance with a program that is provided in advance.

Simply speaking, the controller section **3031** exchanges various kinds of information, such as print commands, with a printer driver of a personal computer PC, with a CPU not shown in the drawings successively executing various processes in accordance with a processing program stored in a memory, receives image data, such as text, to be formed as an

image (printed) on the recording paper, and temporarily stores the image data in a memory not shown in the drawings. Since the image data (image information signal) received from the personal computer PC is so-called RGB data of red (R), green (G) and blue (B), the controller section 3031 reads the data from the memory and passes it to the engine controller 3032 while converting this data into so-called YMCK image data of yellow (Y), magenta (M), cyan (C) and black (K) that can be printed.

With the CPU 3033 following the control program stored in the ROM 3034, the engine controller 3032 receives the image data page by page, for example, from the controller section 3031 and temporarily stores it in a main unit memory 3035, and an image based on this image data is formed on the recording paper by exchanging various kinds of information with the image recording device 3010 and the paper carry device 3020 while using a RAM 3036 as a working area. Moreover, when the CPU 3033 performs the image formation control at this time, it lets each component of the apparatus operate optimally by measuring the various processing times with an internal timer function (time measurement means) 3033a.

Thus, when the control unit 3030 receives image data from the personal computer PC or the like, the controller section 3031 outputs image data, which it has converted from RGB data to YMCK data, to the engine controller 3032, while temporarily storing the image data. The CPU 3033 of the engine controller 3032 comprehensively controls the image recording device 3010 and the paper carry device 3020 based on the image data from the controller section 3031 stored in units of pages in the main unit memory 3035. In accordance with this control, the electrostatic latent image formed on the photoconductive drum 3012 based on the image data is developed with toner by the developing cartridge 3014, and this toner image is transferred to and fixed on one or both sides of recording paper that has been carried from the paper cassette 3021 to form an image, and the recording paper is carried to and stacked on the paper discharge table 3029.

It should be noted that in FIG. 32, an I/O interface 3037 is connected between the image recording device 3010, the paper carry device 3020 and the controller section 3031 on the one hand and the engine controller 3032 on the other hand, such that various kinds of information can be exchanged. A D/A converter 3038 and an A/D converter 3039 convert digital signals (D) into analog signals (A) and convert analog signals into digital signals, such that the various kinds of information that the engine controller 3032 exchanges with the image recording device 3010, the paper carry device 3020 and the controller section 3031 can be processed by these.

The developing cartridges 3014 of the image recording device 3010 are provided with a similar external shape, such that they can be accommodated in a plurality of preset spaces 3015a that are partitioned by partitioning frames 3015c that rotate around the rotation shaft 3015b of the developing rotary unit 3015. Based on the print commands included in the image data from the personal computer PC, the CPU (controller) 3033 of the engine controller 3032 lets the developing rotary unit 3015 rotate around the rotation shaft 3015b to switch the developing cartridge 3014 facing the photoconductive drum 3012 and develop the toner image to be formed by transferring and fixing toner on one side or both sides of the recording paper.

For example, by storing in the developing rotary unit 3015 developing cartridges 3014 containing toner of the colors yellow (Y), cyan (C), magenta (M) and black (K) and switching the color of the toner for developing the electrostatic latent image on the photosensitive drum 3012, the image

recording device 3010 can superimpose or select toner of various colors and print color images or monochrome images, based on the received image data.

Moreover, the image recording device 3010 can also perform image formation when toner of the same color is contained in all developing cartridges 3014 and those developing cartridges 3015 are mounted in the developing rotary unit 3014. For example, by mounting four developing cartridges 3014 containing toner of the same color black (K), it is possible to use the apparatus as a special purpose apparatus that successively switches the developing cartridges 3014 developing the electrostatic latent image on the photoconductive drum 3012 and continuously prints monochrome images.

A so-called memory tag 3041 that is overall very compact and thin is adhered to a predetermined outer surface of each of the developing cartridges 3014 by making one side of it adhesive. When the memory tag 3041 is moved to a rotation position (communication position) facing a main unit-side antenna 3051 on the main unit side of the apparatus shown in FIG. 31, then it is arranged at a position along an external cover 3100 of the apparatus main unit, or in other words, it is placed (adhered) on the outer surface of the developing cartridge 3014 in an upright orientation and at a position where it is closest to this external cover 3100 facing it. This memory tag 3041 is designed to store and hold relevant information and to pass the relevant information to the CPU 3033 of the engine controller 3032 by communicating in a noncontacting manner with a send-receive circuit 3052 on the apparatus main unit side via the main unit-side antenna 3051 to exchange various kinds of information. Here, the main unit-side antenna 3051, which is placed in a downward-facing orientation on the apparatus main unit side, is fabricated in substantially the same manner as a later-described developing-side antenna 3043. The main unit-side antenna 3051 is placed within a distance of, for example, 10 mm of the memory tag 3041, so as to be able to communicate in a noncontacting manner with the memory tag 3041. The main unit-side antenna 3051 is connected to a circuit board constituting the send-receive circuit 3052 and performing communication in a noncontacting manner with the memory tag 3041. This send-receive circuit 3052 is connected via the I/O interface 3037 to the CPU 3033 of the engine controller 3032 on the apparatus main unit side.

More specifically, as shown in FIG. 33(a), in the memory tag 3041 on the side of the developing cartridge 3014, a non-contact IC chip 3042 and the developing-side antenna 3043 are mounted on a plastic film and covered by a transparent cover sheet. The non-contact IC chip 3042 stores and holds various kinds of information based on commands from the send-receive circuit 3052 via the main unit-side antenna 3051 and reads relevant information from these various kinds of information, passing on the relevant information to the send-receive circuit 3052. The developing-side antenna 3043 is made by connecting in parallel the non-contact IC chip 3042 and a resonance capacitor 3043a that is formed by etching a metal film, and arranging a planar coil next to these, the planar coil going several times around the non-contact IC chip 3042 and the resonance capacitor 3043a. Thus, by receiving (absorbing) with the developing-side antenna 3043 a high-frequency magnetic field induced via the main unit-side antenna 3051 by high-frequency signals generated with the send-receive circuit 3052 on the apparatus main unit side, it is possible to access the memory tag 3041 quickly and perform an input into the non-contact IC chip 3042, without carrying out an operation of moving a connector and directly connecting it.

As shown in FIG. 33(b), the non-contact IC chip 3042 of the memory tag 3041 includes a rectifier 3044 serving as a DC power source that rectifies the high-frequency magnetic field (high-frequency signals) from the send-receive circuit 3052 on the apparatus main unit side received via the developing-side antenna 3043 and drives the various circuits within the chip, a signal analysis section RF (Radio Frequency) 3045, which analyzes the high-frequency signals of the received high-frequency magnetic field received via the developing-side antenna 3043 and generates a high-frequency magnetic field that can be absorbed by the main unit-side antenna 3051 by generating a high-frequency signal based on the various kinds of signals to be passed to the send-receive circuit 3052 on the apparatus main unit side and inputting this high-frequency signal to the developing-side antenna 3043, a non-volatile memory cell 3046, such as a NAND flash-ROM or the like, that can store and hold information written into it and from which this stored information can be read out from the outside, and a controller 3047, which rewrites the information stored in the memory cell 3046 by exchanging various kinds of signals with the send-receive circuit 3052 on the side of the apparatus main unit via the signal analysis section RF 3045 and passes the stored information that has been read out to the send-receive circuit 3052, while being driven by the DC power source of the interposed rectifier 3044. That is to say, the memory cell 3046 constitutes a storage element, the developing-side antenna 3043 and the main unit-side antenna 3051 constitute a connection link that can be connected to enable communication in a noncontacting manner, the non-contact IC chip 3042 incorporating the memory cell 3046 and the developing-side antenna 3043 constitute a communication means for communication in a noncontacting manner on the side of the developing cartridge 3014, whereas the main unit-side antenna 3051 and the send-receive circuit 3052 constitute a communication means on the apparatus main unit side.

Here, stored and held inside the memory cell 3046 of the non-contact IC chip 3042 are unique ID information, such as a serial number for each memory tag 3041, manufacturing information, such as the date when the developing cartridge 3014 was manufactured or the manufacturing number, destination information specifying the destination of the developing cartridge 3014, model information specifying models to which the developing cartridge 3014 can be mounted, toner information, such as information on the color and the remaining amount of toner contained in the developing cartridge 3014, and various kinds of relevant information, such as the number of recycles or the number of times the developing cartridge 3014 has been mounted and dismounted. Thus, the engine controller 3032 of the control unit 3030 can perform an optimal image formation control, by suitably ascertaining various kinds of information that the CPU 3033 has stored and held in the main unit-side memory 3035, such as the presence and the position of the developing cartridge 3014 in the storage position of the developing rotary unit 3015, or information about the color of the toner of the developing cartridge 3014. Moreover, if an error occurs, the various kinds of information can be useful in finding the cause of the error by displaying and outputting the information to an operation port.

With the CPU 3033 of the engine controller 3032 following a control program in the ROM 3034, the controller 3047 is caused to perform communication in a noncontacting manner with the apparatus main unit side (the send-receive circuit 3052 via the main unit-side antenna 3051) through the developing-side antenna 3043 of the memory tag 3041, and thus the information stored in the memory cell 3046 of the non-

contact IC chip 3042 is rewritten or readout. For example, when turning on the power or while exchanging the developing cartridge 3014, the CPU 3033 performs a rewrite/read-out process, in which the developing rotary unit 3015 is rotated at least once, so that the memory tag 3041 (developing-side antenna 3043) of each of the developing cartridges 3014 comes to face to the main unit-side antenna 3051 for the time necessary for communication in a noncontacting manner. During regular operation, when the CPU 3033 receives a print command of image data, by beginning with the rotation of the developing rotary unit 3015 from the home position, which is the stand-by position shown in FIG. 34, first the developing cartridge 3014K containing the black (K) toner is positioned in the image recording formation position P facing the photoconductive drum 3012 shown in FIG. 35, and the electrostatic latent image formed on the surface of the photoconductive drum 3012 is developed with toner by this developing cartridge 3014K. After that, the CPU 3033 successively positions (switches) the developing cartridge 3014M containing magenta (M) toner, the developing cartridge 3014C containing cyan (C) toner and the developing cartridge 3014Y containing yellow (Y) toner in a similar manner at the image recording formation position P, and forms color toner images based on the image data by letting them carry out toner development so as to transfer and fix the toner image on the recording paper, thus print-processing the image data.

Parallel to this print control or before or after the print control, when the magenta (M) developing cartridge 3014M is positioned in the image recording formation position P, the memory tag 3041 of the black (K) developing cartridge 3014K that has performed the directly preceding developing operation is positioned in the communication position facing the main unit-side antenna 3051, so that the CPU 3033 rewrites and reads out information stored in the memory cell 3046 of this memory tag 3041 by performing contactless information with this memory tag 3041 via the send-receive circuit 3052 on the apparatus main unit side. After this, and before the black (K) developing cartridge 3014K is rotated and moved back to its home position, which is the lowest position, and put into the stand-by state, the respective memory tags 3041 of the magenta (M) developing cartridge 3014M, the cyan (C) developing cartridge 3014C and the yellow (Y) developing cartridge 3014Y are successively positioned in the communication position facing the main unit-side antenna 3051, so that the CPU 3033 rewrites or reads the information stored in the memory cells 3046 of these memory tags 3041. Thus, the CPU 3033 finishes the rewriting and reading of the information stored in the memory cells 3046 of all memory tags 3041, after which it rotates the developing rotary unit 3015 to its home position to put it into the stand-by state.

Here, the non-contact IC chip 3042, which incorporates the rectifier 3044, the signal analysis section RF 3045, the memory cell 3046, and the controller 3047, is connected in parallel to the resonance capacitor 3043a, and the memory tag 3041 performs communication in a noncontacting manner through the antennas 3043 and 3051 with the send-receive circuit 3052 on the apparatus main unit side, so that its internal elements, namely the resonance capacitor 3043a and the non-contact IC chip 3042 are easily affected by the environment in which the memory tag 3041 is placed. For example, when attempting to perform communication in a noncontacting manner while the memory tag 3041 is exposed to a high temperature and heated up, the distance over which communication in a noncontacting manner is possible becomes shorter the higher the temperature is above room temperature, as shown in FIG. 36. Moreover, the memory tag 3041 is stuck

to the outer surface of the developing cartridge 3014 rotating away from the communication position where the memory tag 3041 faces the main unit-side antenna 3051. The developing roller 3014a, which faces the photoconductive drum 3012 across a tiny gap, protrudes from the outer surface of the developing cartridge 3014, so that there is a limit to how close the developing cartridge 3014 can be brought to the main unit-side antenna 3051.

On the other hand, below the developing rotary unit 3015 that rotates and moves the developing cartridges 3014, the laser beam scanning device (exposing unit) 3011, which forms the electrostatic latent image through scanning/exposing the photoconductive drum 3012 by irradiating a laser beam L1 based on the image data, is disposed at a position that is close, in accordance with the miniaturization of the image forming apparatus, as is shown in FIG. 34 and FIG. 35. This laser beam scanning device 3011, which is placed with the purpose of quickly exposing and forming an electrostatic latent image on the photoconductive drum 3012, scans the laser beam L1 by swinging (reflecting) it along the axial direction (main scanning direction) of the photoconductive drum 3012 by rotating an internal polygon mirror 3011a at high speed. That is to say, the laser beam scanning device 3011 incorporates a polygon motor (scanner motor) 3011b, which rotates the polygon mirror 3011a at high speed, as well as a driver section 3011c controlling the generation/irradiation of the laser beam L1 and the driving of the polygon motor 3011b, so that it is a heat-generating member (heat source) that becomes hotter the longer it is continuously driven.

Therefore, if the memory tag 3041, which is placed on the outer surface of the developing cartridge 3014, is positioned for a long time in the vicinity A of a position facing the polygon motor 3011b or the driver section 3011c of the laser beam scanning device 3011 during continuous image formation or when being rotated and moved into the home position for stand-by after a continuous operation has been finished, then the memory tag 3041 is heated up. When this memory tag 3041 is rotated and moved to the communication position where it faces the main unit-side antenna 3051 to carry out communication in a noncontacting manner before its temperature has returned to approximately room temperature, there is the risk that a sufficient sensitivity cannot be attained, that the rewriting and reading of the information stored in the memory cell 3046 with the send-receive circuit 3052 on the apparatus main unit side cannot be accomplished efficiently (without a drop in the processing speed or the like), and that errors occur during the rewriting or reading of information stored in the memory cell 3046 due to connection faults (communication faults). Furthermore, also the developing roller 3014a of the developing cartridge 3014 is in a state where its outer circumferential surface on which the contained toner adheres is exposed to the outside, so that when this toner is unnecessarily heated, there is the risk that the developing quality of the electrostatic latent image on the photoconductive drum 3012 or the quality of the image transfer onto the intermediate image transfer belt 3016 or the like drops.

Accordingly, the memory tags 3041 are arranged on the outer surface of the developing cartridge 3014 at a position that is removed in the axial direction of the rotation shaft 3015b of the developing rotary unit 3015 from the vicinity A of the position where it faces the laser beam scanning device 3011, as shown in FIG. 34(b) and FIG. 35(b). In addition to this, the polygon motor 3011b and the driver section 3011c of the laser beam scanning device 3011 are laid out such that at a timing when the black (K) developing cartridge 3014K is positioned in the home position in which it is in stand-by at

the lowest position, they are positioned between its developing roller 3014a and its memory tag 3041 in terms of the rotation direction of the developing rotary unit 3015, as shown in FIG. 34, and at a timing when one of the developing cartridges 3014 is positioned in the image recording formation position P facing the photoconductive drum 3012, they are positioned between the two developing cartridges 3014 positioned on the lower side of the developing rotary unit 3015, or in other words, between the developing roller 3014a and the memory tag 3041, as shown in FIG. 35. That is to say, the memory tags 3041 are removed in the axial direction and the rotation direction of the developing rotary unit 3015 from the position on the outer surface of the developing cartridge 3014 that faces the vicinity A of the position near the polygon motor 3011b and the driver section 3011c of the laser beam scanning device 3011, which are heat-generating members. Moreover, also the developing rollers 3014a are arranged at a position that is removed in the rotation direction from the position opposite the vicinity A of this position. It should be noted that 3014d in FIG. 34 and FIG. 35 denotes an aperture section through which the laser beam L1 is irradiated from the laser beam scanning device 3011.

Thus, it is possible to let the memory tag 3041 and the developing roller 3014a of the developing cartridges 3014 rotating and stopping during stand-by or during the developing operation rest at a position that is removed from the vicinity A of the position facing the polygon motor 3011b and the driver section 3011c of the laser beam scanning device 3011, so that it is possible to avoid that the memory tag 3041 receives the heat emitted from the laser beam scanning device 3011 and unnecessarily heats up when the vicinity A of this position heats up considerably above room temperature due to continuous driving of the laser beam scanning device 3011. Consequently, even when directly before the developing cartridge 3014 has come close to the laser beam scanning device 3011, it can be avoided that this becomes a cause for a drop in the image quality of the toner image made by adhering the toner on the outer circumferential surface of the developing roller 3014a to the electrostatic latent image on the photoconductive drum 3012 or the image quality of this toner image transferred onto the intermediate image transfer belt 3016 or the like. Furthermore, when reading or rewriting the stored information by accessing the memory tag 3041 of the developing cartridge 3014 through communication in a noncontacting manner, it is possible to rewrite or read the information stored in the memory cell 3046 efficiently, without errors and without a drop in sensitivity.

Thus, in this embodiment, by removing the memory tag 3041 of the developing cartridge 3014 in its rotation direction and its axial direction from the vicinity A of the position where it faces the polygon motor 3011b or the driver section 3011c of the laser beam scanning device 3011, it can perform communication in a noncontacting manner with the send-receive circuit 3052 via the main unit-side antenna 3051 without being thermally affected by the laser beam scanning device 3011 (without the occurrence of sensitivity faults), so that the reading out and rewriting of information stored in the memory cell 3046 can be accomplished efficiently and without errors. Consequently, the processes of rewriting or reading the various kinds of information in the memory tags 3041 of each of the developing cartridges 3014 can be carried out accurately and speedily, and the information that is necessary for the drive control of the various components of the apparatus can be made accessible in a smooth manner. Furthermore, by removing also the developing roller 3014a of the developing cartridge 3014 in its rotation direction from the vicinity A of this position at this time, the toner development

of the electrostatic latent image on the photoconductive drum **3012** can be performed with high accuracy without being thermally affected by the laser beam scanning device **3011**, and an image of high quality can be formed.

As an alternative form of this embodiment, the present invention can also be applied to cases in which, instead of an antenna for communication in a noncontacting manner as in the present embodiment, a connector **3072** provided with electrode terminals **3071** is connected with the send-receive circuit **3052** on the apparatus main unit side, and a memory tag **3073** with exposed electrode terminals not shown in the drawings is placed on the side of the developing cartridge **3014**, as shown in FIG. 37, so that during communication, the connector **3072** approaches the memory tag **3073** and the electrode terminals **3071** are pressed against each other, thereby establishing a connection allowing communication by contact. In this case, as in the above-described embodiment, the memory tag **3073** on the outer surface of the developing cartridge **3014** in the communication position establishes a conductive connection with the connector **3072** and can perform the processes of rewriting and reading various kinds of information in the memory cell with high reliability, without being thermally affected by the laser beam scanning device **3011**.

Thus, with this fourth embodiment, the storage elements on the outer surfaces of the developing cartridges can be removed in either the rotation direction or the axial direction or both from the position where they face the heat-generating members that are heat sources inside the apparatus main unit during the time when the rotation of the developing cartridges is stopped, and they can perform the reading and writing of the information stored in the storage element and the communication processing without being thermally affected by these heat-generating members. Consequently, it is possible to avoid that errors occur during the reading and writing of information stored in the storage element, or that the performance of the communication processing of this stored information drops. As a result, by accessing the storage element of each developing cartridge with high reliability, it is possible to smoothly utilize the information stored in the storage elements for the drive control of the image processing or the like.

The preceding was an explanation of a fourth embodiment, but the present invention is not limited to this embodiment, and needless to say, the present invention can be embodied through various forms within the technical scope of the invention.

Overview of Image Forming Apparatus of Fifth Embodiment

The following is an explanation of a fifth embodiment of the present invention, with reference to the drawings. FIGS. 38 to 41 are diagrams showing an embodiment of an image forming apparatus according to the present invention.

In FIG. 38 and FIG. 39, the image forming apparatus is a printer that is used by connecting it to an external device such as a personal computer PC that creates and outputs images of text or the like. This image forming apparatus includes an image recording device **4010** that records and forms images on one side or both sides of recording paper (recording medium) through electrophotography by reading in image data of text or the like to be image-formed, a paper carry device **4020** that carries a plurality of stacked recording papers to the image recording device **4010** and carries the recording paper on which an image has been recorded and formed out of the apparatus, stacking the recording paper, and a control unit **4030** that is connected to a personal computer

PC and makes print-outs by forming images on the recording paper through comprehensive control of the overall apparatus including the image recording device **4010** and the paper carry device **4020** in accordance with the image data that has been received.

Simply speaking, the image recording device **4010** includes, as shown in FIG. 38, a laser beam scanning device **4011** scanning a laser beam **L1** based on image data, a photoconductive drum (bearing member) **4012** on the surface of which an electrostatic latent image is exposed and formed based on image data that is irradiated and scanned with the laser beam **L1** from the laser beam scanning device **4011**, a charge device **4013** charging the outer circumferential surface of the photoconductive drum **4012** such that an electrostatic latent image can be formed by irradiating the laser beam **L1**, a developing cartridge **4014** (shown only at one place) for each of the colors, which contains yellow (Y), cyan (C), magenta (M) or black (K) toner and selectively lets the contained toner adhere to perform toner development of the electrostatic latent image on the surface of the photoconductive drum **4012** by rotating, in synchronization, developing rollers **4014a** facing the surface of the photoconductive drum **4012** across a gap, a developing rotary unit **4015** holding the developing cartridges **4014** in preset spaces **4015a** for each color and rotating them around a rotation shaft **4015b**, an intermediate image transfer belt (intermediate image transfer member) **4016**, which can receive the toner image developed on the photoconductive drum **4012** so that a toner image (monochrome image or color image) is formed on it that can be transferred and recorded on recording paper, an image transfer roller **4017** transferring the toner image carried on the intermediate image transfer belt **4016** by applying a contact pressure (nip) such that the recording paper carried up to it is sandwiched between the image transfer roller **4017** and the intermediate image transfer belt **4016**, and carrying the recording paper downstream while clamping the recording paper, a pair of fixing rollers **4018** fixing the toner image by applying heat and contact pressure to the recording paper onto which the toner image has been transferred and which has been carried up to them, and clamping and carrying the recording paper further downstream, and a waste toner tank **4019** collecting and accumulating toner that has remained on the photoconductive drum **4012** with a blade **4019a**. It should be noted that toner is supplied to the developing roller **4014a** of the developing cartridge **4014** by pressing a supply roller **4014b** rotating within the toner containing space of the developing cartridge **4014** against the developing roller **4014a**. Also the unit of the intermediate image transfer belt **4016** is provided with a waste toner tank in which the toner remaining on the belt **4016** is collected with a blade and stored.

Thus, in the image recording device **4010**, the developing cartridge **4014** inside the developing rotary unit **15** that has been switched in accordance with the image data develops with toner the electrostatic latent image based on the image data formed on the surface of the photoconductive drum **4012** with the laser beam scanning device **4011**. And after that, the toner image on the photoconductive drum **4012** is subjected to a primary image transfer onto the intermediate image transfer belt **4016** and then subjected to a secondary image transfer onto recording paper that has been carried with the paper carry device **4020** and recorded, after which it is fixed by applying heat and pressure with the pair of fixing rollers **4018**, thus accomplishing image formation.

Here, with this developing cartridge **4014**, when the developing roller **4014a** that rotates while facing the photoconductive drum **4012** across the gap transfers and adheres the contained toner to the surface of the photoconductive drum **4012**,

101

a small fraction of the toner is scattered and drifts to the downstream side in the rotation direction, so that an exhaust duct 4060 sucks in air with a suction fan not shown in the drawings from a suction opening 4061 above the vicinity of the position where the developing roller 4014a opposes the photoconductive drum 4012, and exhausts the air via an exhaust path 4062 from an exhaust opening 4063. The toner included in the air that is sucked in is adsorbed and removed by a filter 4064 arranged midway in the exhaust path 4062, thereby preventing that the outside of the apparatus is polluted.

Simply speaking, the paper carry device 4020 includes, as shown in FIG. 38, a paper cassette 4021, which is removably set in a lower section of the apparatus main unit and in which a plurality of sheets of recording paper are stacked, a pick-up roller 4022, which picks up the uppermost recording paper by rotating while being pressed against the stack of recording paper that has been elevated with an elevating plate 4021a at the bottom surface of the paper cassette 4021, thereby feeding the recording paper to a carry path f, a pair of relay carry rollers 4023a and 4023b, which receive the recording paper that is fed to them by the pick-up roller 4022 and clamp and carry the recording paper to the carry path f further downstream, a pair of registration rollers 4024, which receive the recording paper in the carry path f that is carried by the pair of relay carry rollers 4023a and 4023b and clamp and carry the recording paper to an image recording formation position given by the intermediate image transfer belt 4016 and the image transfer roller 4017 of the image recording device 4010, and a pair of paper discharge rollers 4025a and 4025b, which receive the recording paper on one side of which a fixed image has been formed by carrying the recording paper along the carry path f from the pair of registration rollers 4024, between the intermediate image transfer belt 4016 and the image transfer roller 4017 and between the pair of fixing rollers 4018, and which carries, discharges and stacks the recording paper on a paper discharge table 4029 at the top portion of the apparatus main unit. It should be noted that the intermediate image transfer belt 4016, the image transfer roller 4017 and the pair of fixing rollers 4018 of this image recording device also have the function of carrying the recording paper, so that they also constitute a part of the paper carry device 4020.

Thus, after the recording paper that has been picked up from the paper cassette 4021 with the pick-up roller 4022 has been passed on via the pair of relay carry rollers 4023a and 4023b to the pair of registration rollers 4024, the paper carry device 4020 supplies the recording paper to the image recording formation position at which the recording paper is pressed against by the intermediate image transfer belt 4016 and the image transfer roller 4017 such that the pair of registration rollers 4024 is synchronized with the operation of the image recording device 4010. The recording paper, on which the toner image on the intermediate image transfer belt 4016 has been transferred and recorded, and the image based on the image data has been fixed (recording formation) with the pair of fixing rollers 4018, is received by the pair of paper discharge rollers 4025a and 4025b and is carried and ejected and stacked on the paper discharge table 4029.

Here, this paper carry device 4020 includes a reverse carry path r and a pair of intermediate carry rollers 4027 disposed on this path r for turning over recording paper on one side of which an image has been formed and feeding it to the carry path f on the upstream side of the pair of registration rollers 4024. The recording paper, which has been fed into the reverse carry path r by inverting the rotation of the pair of paper discharge rollers 4025a and 4025b is received by the

102

pair of intermediate carry rollers 4027 and passed on to the pair of registration rollers 4024, so that image formation on both sides of the recording paper is possible. Moreover, the paper carry device 4020 includes a manual feed path m and a pair of manual feed rollers 4028 disposed on this path m for manually feeding recording paper into the carry path f on the upstream side of the pair of registration rollers 4024. Image formation on one side or both sides of the recording paper is possible by receiving the recording paper inserted into this manual feed path m with the pair of manual feed rollers 4028 and passing it to the pair of registration rollers 4024.

As shown in FIG. 39, the control unit 4030 includes a controller section 4031 and an engine controller 4032 implemented on a circuit board mounted inside the apparatus main unit. These perform various kinds of data process control and drive control of the various components of the apparatus in accordance with a program that is provided in advance.

Simply speaking, the controller section 4031 exchanges various kinds of information, such as print commands, with a printer driver of a personal computer PC, with a CPU not shown in the drawings successively executing various processes in accordance with a processing program stored in a memory, receives image data, such as text, to be formed as an image (printed) on the recording paper, and temporarily stores the image data in a memory not shown in the drawings. Since the image data (image information signal) received from the personal computer PC is so-called RGB data of red (R), green (G) and blue (B), the controller section 4031 reads the data from the memory and passes it to the engine controller 4032 while converting this data into so-called YMCK image data of yellow (Y), magenta (M), cyan (C) and black (K) that can be printed.

With the CPU 4033 following the control program stored in the ROM 4034, the engine controller 4032 receives the image data page by page, for example, from the controller section 4031 and temporarily stores it in a main unit memory 4035, and an image based on this image data is formed on the recording paper by exchanging various kinds of information with the image recording device 4010 and the paper carry device 4020 while using a RAM 4036 as a working area. Moreover, in this situation, when the CPU 4033 performs the image formation control, it lets each section of the apparatus operate optimally by measuring the various processing times with an internal timer function (time measurement means) 4033a.

Thus, when the control unit 4030 receives image data from the personal computer PC or the like, the controller section 4031 outputs image data, which it has converted from RGB data to YMCK data, to the engine controller 4032, while temporarily storing the image data. The CPU 4033 of the engine controller 4032 comprehensively controls the image recording device 4010 and the paper carry device 4020 based on the image data from the controller section 4031 stored in units of pages in the main unit memory 4035. In accordance with this control, the electrostatic latent image formed on the photoconductive drum 4012 based on the image data is developed with toner by the developing cartridge 4014, and this toner image is transferred to and fixed on one or both sides of recording paper that has been carried from the paper cassette 21 to be form an image, and the recording paper is carried to and stacked on the paper discharge table 4029.

It should be noted that in FIG. 39, an I/O interface 4037 is connected between the image recording device 4010, the paper carry device 4020 and the controller section 4031 on the one hand and the engine controller 4032 on the other hand, such that various kinds of information can be exchanged. A D/A converter 4038 and an A/D converter 4039 convert digi-

103

tal signals (D) into analog signals (A) and convert analog signals into digital signals, such that the various kinds of information that the engine controller 4032 exchanges with the image recording device 4010, the paper carry device 4020 and the controller section 4031 can be processed by these.

The developing cartridges 4014 of the image recording device 4010 are provided with a similar external shape, such that they can be accommodated in a plurality of preset spaces 4015a that are partitioned by partitioning frames 4015c that rotate around the rotation shaft 4015b of the developing rotary unit 4015. Based on the print commands included in the image data from the personal computer PC, the CPU (controller) 4033 of the engine controller 4032 lets the developing rotary unit 4015 rotate around the rotation shaft 15b to switch the developing cartridge 4014 facing the photoconductive drum 4012 and develop the toner image formed by transferring and fixing toner on one side or both sides of the recording paper.

For example, by storing in the developing rotary unit 4015 developing cartridges 4014 containing toner of the colors yellow (Y), cyan (C), magenta (M) and black (K) and switching the color of the toner for developing the electrostatic latent image on the photosensitive drum 4012, the image recording device 4010 can superimpose or select toner of various colors and print color images or monochrome images, based on the received image data.

Moreover, the image recording device 4010 can also perform image formation when toner of the same color is contained in all developing cartridges 4014 and those developing cartridges 4014 are mounted in the developing rotary unit 4015. For example, by mounting four developing cartridges 4014 containing toner of the same color black (K), it is possible to use the apparatus as a special purpose apparatus that successively switches the developing cartridges 4014 developing the electrostatic latent image on the photoconductive drum 4012 and continuously prints monochrome images.

A so-called memory tag 4041 that is overall very compact and thin is adhered to a predetermined outer surface of each of the developing cartridges 4014 by making one side of it adhesive. When the memory tag 4041 is moved to a rotation position (communication position) facing a main unit-side antenna 4051 on the main unit side of the apparatus shown in FIG. 38, then it is arranged at a position along an external cover 4100 of the apparatus main unit, or in other words, it is placed (stuck) on the outer surface of the developing cartridge 4014 in an upright orientation and at a position where it is closest to this external cover 4100 facing it. This memory tag 4041 is designed to store and hold relevant information and to pass the relevant information to the CPU 4033 of the engine controller 4032 by communicating in a noncontacting manner with a send-receive circuit 4052 on the apparatus main unit side via the main unit-side antenna 4051 to exchange various kinds of information. Here, the main unit-side antenna 4051, which is placed in a downward-facing orientation on the apparatus main unit side, is fabricated in substantially the same manner as a later-described developing-side antenna 4043. The main unit-side antenna 4051 is placed within a distance of, for example, 10 mm of the memory tag 4041, so as to be able to communicate in a noncontacting manner with the memory tag 4041. The main unit-side antenna 4051 is connected to a circuit board constituting the send-receive circuit 4052 and performing communication in a noncontacting manner with the memory tag 4041. This send-receive circuit 4052 is connected via the I/O interface 4037 to the CPU 4033 of the engine controller 4032 on the apparatus main unit side.

104

More specifically, as shown in FIG. 40(a), in the memory tag 4041 on the side of the developing cartridge 4014, a non-contact IC chip 4042 and the developing-side antenna 4043 are mounted on a plastic film and covered by a transparent cover sheet. The non-contact IC chip 4042 stores and holds various kinds of information based on commands from the send-receive circuit 4052 via the main unit-side antenna 4051 and reads relevant information from these various kinds of information, passing on the relevant information to the send-receive circuit 4052. The developing-side antenna 4043 is made by connecting in parallel the non-contact IC chip 4042 and a resonance capacitor 4043a that is formed by etching a metal film, and arranging a planar coil next to these, the planar coil going several times around the non-contact IC chip 4042 and the resonance capacitor 4043a. Thus, by receiving (absorbing) with the developing-side antenna 4043 a high-frequency magnetic field induced via the main unit-side antenna 4051 by high-frequency signals generated with the send-receive circuit 4052 on the apparatus main unit side, it is possible to access the memory tag 4041 quickly and perform an input into the non-contact IC chip 4042, without carrying out an operation of moving a connector and directly connecting it.

As shown in FIG. 40(b), the non-contact IC chip 4042 of the memory tag 4041 includes a rectifier 4044 serving as a DC power source that rectifies the high-frequency magnetic field (high-frequency signals) from the send-receive circuit 4052 on the apparatus main unit side received via the developing-side antenna 4043 and drives the various circuits within the chip, a signal analysis section REF (Radio Frequency) 4045, which analyzes the high-frequency magnetic field received via the developing-side antenna 4043 and generates a high-frequency magnetic field that can be absorbed by the main unit-side antenna 4051 by generating a high-frequency signal based on the various kinds of signals to be passed to the send-receive circuit 4052 on the apparatus main unit side and inputting this high-frequency signal to the developing-side antenna 4043, a non-volatile memory cell 4046, such as a NAND flash-ROM or the like, that can store and hold information written into it and from which this stored information can be read out from the outside, and a controller 4047, which rewrites the information stored in the memory cell 4046 by exchanging various kinds of signals with the send-receive circuit 4052 on the side of the apparatus main unit via the signal analysis section REF 4045 and passes the stored information that has been read out to the send-receive circuit 4052, while being driven by the DC power source of the interposed rectifier 4044. That is to say, the memory cell 4046 constitutes a storage element, the developing-side antenna 4043 and the main unit-side antenna 4051 constitute a connection link that can be connected to enable communication in a noncontacting manner, the non-contact IC chip 4042 incorporating the memory cell 4046 and the developing-side antenna 4043 constitutes a communication means for communication in a noncontacting manner on the side of the developing cartridge 4014, whereas the main unit-side antenna 4051 and the send-receive circuit 4052 constitute a communication means on the apparatus main unit side.

Here, stored and held inside the memory cell 4046 of the non-contact IC chip 4042 are unique ID information, such as a serial number for each memory tag 4041, manufacturing information, such as the date when the developing cartridge 4014 was manufactured or the manufacturing number, destination information specifying the destination of the developing cartridge 4014, model information specifying models to which the developing cartridge 4014 can be mounted, toner

information, such as information on the color and the remaining amount of toner contained in the developing cartridge 4014, and various kinds of relevant information, such as the number of recycles or the number of times the developing cartridge 4014 has been mounted and dismounted. Thus, the engine controller 4032 of the control unit 4030 can perform an optimal image formation control, by suitably ascertaining various kinds of information that the CPU 4033 has stored and held in the main unit-side memory 35, such as the presence and the position of the developing cartridge 4014 in the storage position of the developing rotary unit 4015, or information about the color of the toner of the developing cartridge 4014. Moreover, if an error occurs, the various kinds of information can be useful in finding the cause of the error by displaying/outputting the information to an operation port.

With the CPU 4033 of the engine controller 4032 following a control program in the ROM 4034, the controller 4047 is caused to perform communication in a noncontacting manner with the apparatus main unit side (the send-receive circuit 4052 via the main unit-side antenna 4051) through the developing-side antenna 4043 of the memory tag 4041, and thus the information stored in the memory cell 4046 of the non-contact IC chip 4042 is rewritten or read out. For example, when turning on the power or while exchanging the developing cartridge 4014, the CPU 4033 performs a rewrite/read-out process, in which the developing rotary unit 4015 is rotated at least once, so that the memory tag 4041 (developing-side antenna 4043) of each of the developing cartridges 4014 comes to face the main unit-side antenna 4051 for the time necessary for communication in a noncontacting manner. Moreover, when the CPU 4033 receives a print command of image data during ordinary operation, the developing cartridge 4014K containing the black (K) toner is first positioned in the image recording formation position P where it faces the photoconductive drum 4012 shown in FIG. 41 by starting to rotate the developing rotary unit 4015 from the home position, in which the black (K) developing cartridge 4014K is at the lowest position, and toner development of the electrostatic latent image formed on the surface of the photoconductive drum 4012 is carried out with this developing cartridge 4014K. After that, the CPU 4033 successively positions (switches) the developing cartridge 4014M containing magenta (M) toner, the developing cartridge 4014C containing cyan (C) toner, and the developing cartridge 4014Y containing yellow (Y) toner in a similar manner at the image recording formation position P, and forms color toner images based on the image data by letting them carry out toner development so as to transfer and fix the toner image on the recording paper, thus print-processing the image data.

Parallel to this print control or before or after the print control, when the magenta (M) developing cartridge 4014M is positioned in the image recording formation position P, the memory tag 4041 of the black (K) developing cartridge 4014K that has performed the directly preceding developing operation is positioned in the communication position facing the main unit-side antenna 4051 as shown in FIG. 41, so that the CPU 4033 rewrites and reads out information stored in the memory cell 4046 of this memory tag 4041 by performing contactless information with this memory tag 4041 via the send-receive circuit 4052 on the apparatus main unit side. After this, and before the black (K) developing cartridge 4014K is rotated and moved back to its home position, which is the lowest position, and put into the stand-by state, the respective memory tags 4041 of the magenta (M) developing cartridge 4014M, the cyan (C) developing cartridge 4014C and the yellow (Y) developing cartridge 4014Y are successively positioned in the communication position facing the

main unit-side antenna 4051, so that the CPU 4033 rewrites or reads the information stored in the memory cells 4046 of these memory tags 4041. Thus, the CPU 4033 finishes the rewriting and reading of the information stored in the memory cells 4046 of all memory tags 4041, after which it rotates the developing rotary unit 4015 to its home position to put it into the stand-by state.

Here, the memory tag 4041 performs the reading and rewriting of the information stored in the memory cell 4046 of the non-contact IC chip 4042 by performing communication in a noncontacting manner, in which it exchanges signals with the main unit-side antenna 4051 via the developing-side antenna 4043, so that the information stored in the memory cell 4046 may be unnecessarily rewritten or deleted and corrupted directly or indirectly by noise of or above a certain intensity. In this context, the risk that the noise easily intrudes into the memory cell 4046 from the developing-side antenna 4043 and thus indirectly makes the information stored in the memory cell 4046 inaccurate is greater than the risk that the noise directly intrudes into the memory cell 4046. In particular, the memory tag 4041, in which the developing-side antenna 4043 is formed in the same plane as the non-contact IC chip 4042 incorporating the memory cell 4046, is stuck to the outer surface of the developing cartridge 4014, so that depending on the rotation position of the developing cartridge 4014, it can assume an orientation in which it is approximately facing the source of the noise and the noise from there can easily intrude (may be easily picked up from the developing-side antenna 4043).

On the other hand, regarding the devices arranged around the developing rotary unit 4015, the roller-shaped charge device 4013 contacts the outer circumferential surface of the photoconductive drum 4012 and applies a high voltage to it, thereby charging the photoconductive drum 4012 to a potential at which an electrostatic latent image to which toner adheres by scanning a laser beam L1 with the laser beam scanning device 4011 is formed (to a high voltage at which no toner adheres before exposure), so that there is the possibility that the location where the charge device 4013 applies a high voltage to the photoconductive drum 4012 or the photoconductive drum 4012 itself emit noise to their surroundings. That is to say, the photoconductive drum 4012 itself constitutes a high-voltage member, of the charged members, taking on a voltage equal or greater than that which is necessary for the adherence of toner, and the charge device 4013 constitutes a high-voltage member, of the voltage-applying members, taking on a voltage equal or greater than that which is necessary for the adherence of toner. Moreover, by letting a roller member (not shown in the drawings) contact an electrode portion exposed at the edge of the belt and rotating the roller member while applying a high voltage, the intermediate image transfer belt 4016 is charged to a high voltage at which the primary image transfer of the toner image on the surface of the photoconductive drum 4012 is possible (at which the toner is attracted), so that there is the possibility that the location where the roller member applies a high voltage to the intermediate image transfer belt 4016 or the intermediate image transfer belt 4016 itself emit noise to their surroundings. That is to say, the intermediate image transfer belt 4016 itself constitutes a high-voltage member, of the charged members, taking on a voltage equal or greater than that which is necessary for the image transfer, and the roller member constitutes a high-voltage member, of the voltage-applying members, taking on a voltage equal or greater than that which is necessary for the image transfer. Here, the case is explained that a method is adopted in which the photoconductive drum 4012 is charged by contacting it with a roller-shaped member

107

serving as the charge device 4013, but the present invention can also be applied when a method is adopted in which the photoconductive drum 4012 is charged by applying a high voltage to an electrode wire.

For this reason, the possibility is high that at a timing in which the memory tag 4041 placed on the outer surface of the developing cartridge 4014 is in a location facing the photoconductive drum 4012 and the intermediate image transfer belt 4016, or at a timing in which it is in an orientation facing the locations where the photoconductive drum 4012 and the intermediate image transfer belt 4016 are charged, the memory tag 4041 picks up noise emitted from these, and the risk that it is in a state facing a noise-emitting location continuously for a certain period of time and picks up the noise emitted from there is highest in particular during development when the photoconductive drum 4012 faces the developing roller 4014a of the developing cartridge 4014.

Accordingly, blocking members 4071 and 4072 that are made of a conductive material, such as sheet metal, and connected to ground are arranged around the developing rotary unit 4015 on both the upstream side and the downstream side in the rotation direction of the developing cartridge 4014 adjacent to the outer circumferential surface of the photoconductive drum 4012. That is to say, the blocking members 4071 and 4072 are arranged between the rotation trajectory of the memory tags 4041 on the outer surface of the developing cartridges 4014 and the location where the photoconductive drum 4012 faces the intermediate image transfer belt 4016 as well as the location where these are charged, and when the rotation of the developing cartridge 4014 is stopped and the development operation is carried out, the blocking members 4071 and 4072 face the memory tag 4041 opposing them in a substantially planar orientation, so that they are placed between the memory tag 4041 and the noise source. It should be noted that the developing rollers 4014a of the developing cartridges 4014 oppose the photoconductive drum 4012 across a tiny gap, so that the blocking members 4071 and 4072 are placed at positions that are so close to the photoconductive drum 4012 that this opposition is not hindered.

Thus, even when noise is emitted from the location where the photoconductive drum 4012 faces the intermediate image transfer belt 4016 or the location where these are charged, this noise is absorbed by the blocking members 4071 and 4072 and can be restricted so that it does not reach the memory tags 4041 (the developing-side antennas 4043 or the memory cells 4046), and it can be prevented that the information stored in the memory cells 4046 is adversely affected by being rewritten (destroyed) or deleted.

Thus, in the present embodiment, it can be prevented from the beginning that noise emitted from the location where the photoconductive drum 4012 faces the intermediate image transfer belt 4016 or the location where these are charged intrudes into the memory tags 4041 rotating and moving on the outer surface of the developing cartridges 4014, and it can be avoided that the information stored in the memory cells 4046 is rewritten or deleted so that it becomes unusable. Consequently, the reliability of the information stored in the memory tags 4041 (memory cells 4046) on the outer surface of the developing cartridges 4014 can be ensured even when the photoconductive drum 4012 is designed to have a smaller diameter and the charge device 4013 is placed at a position near the developing rotary unit 4015 (developing cartridges 4014), or similarly, when the intermediate image transfer belt 4016 is arranged near the developing rotary unit 4015. As a result, accurate information stored in the memory tags 4041 can be utilized smoothly for the drive control.

108

With the present embodiment, it can be prevented from the beginning that the noise from the high-voltage members intrudes into the storage elements or antennas rotating and moving on the outer surface of the developing cartridges, so that it can be avoided that the information stored in these storage elements is rewritten or deleted and becomes unusable. Consequently, it is possible to utilize the information stored in the storage elements with high reliability, and the information stored in the storage elements can be utilized smoothly for the drive control of the image processing or the like.

The preceding was an explanation of an embodiment of the present invention, but the present invention is not limited to this embodiment, and needless to say, the present invention can be embodied through various forms within the technical scope of the invention. For example, in the present embodiment, an example was explained in which a configuration is adopted in which a plurality of developing cartridges 4014 are accommodated in the developing cartridge unit 4015 and an intermediate image transfer belt 4016 is provided. However, there is no limitation to this, and the present invention can also be favorably applied to cases where a member is provided that charges the toner in order to transfer the toner.

25 Overview of Image Forming Apparatus of Sixth Embodiment

Next, using FIG. 42, an overview of a laser beam printer (hereinafter, also referred to as "printer") 5010 serving as an example of an image forming apparatus is described. FIG. 42 is a diagram showing the main structural components constituting the printer 5010. It should be noted that in FIG. 42, the vertical direction is indicated by the arrows, and, for example, a paper supply tray 5092 is arranged at a lower section of the printer 5010 and a fixing unit 5090 is disposed at an upper section of the printer 5010.

As shown in FIG. 42, the printer 5010 according to the present embodiment includes a charging unit 5030, an exposing unit 5040, a YMCK developing unit 5050 serving as an example of a rotating member, a primary image transfer unit 5060, an intermediate image transfer member 5070, and a cleaning unit 5075, which are arranged along the rotation direction of a photoconductor 5020. The printer 5010 further includes a secondary image transfer unit 5080, a fixing unit 5090, a displaying unit 5095 constituted by a liquid-crystal panel and serving as a means for giving notifications to the user, and a control unit 5100 for controlling these units and managing the operations of the printer.

The photoconductor 5020 has a hollow cylindrical conductive base and a photoconductive layer formed on the outer circumferential surface of the conductive base, and is rotatable around its center axis. In the present embodiment, the photoconductor 5020 rotates clockwise, as indicated by the arrow in FIG. 42.

55 The charging unit 5030 is a device for charging the photoconductor 5020. The exposing unit 5040 is a device for forming a latent image on the charged photoconductor 5020 by irradiating a laser beam thereon. The exposing unit 5040 includes, for example, a semiconductor laser, a polygon mirror, and an F-0 lens, and irradiates a modulated laser beam onto the charged photoconductor 5020 in accordance with image signals that have been input from a host computer, not shown in the drawings, such as a personal computer or a word processor.

60 The YMCK developing unit 5050 is a device for developing the latent image formed on the photoconductor 5020 using toner T, which is an example of a developer contained in

109

developing containers, that is, black (K) toner contained in a black developing container **5051**, magenta (M) toner contained in a magenta developing container **5052**, cyan (C) toner contained in a cyan developing container **5053**, and yellow (Y) toner contained in a yellow developing container **5054**.

By rotating the YMCK developing unit **5050** with the four developing containers **5051**, **5052**, **5053**, and **5054** mounted to it, it is possible to move the positions of these four developing containers **5051**, **5052**, **5053**, and **5054**. That is to say, the YMCK developing unit **5050** holds the four developing containers **5051**, **5052**, **5053** and **5054** with four holding sections **5055a**, **5055b**, **5055c** and **5055d**, which are examples of mounting and dismounting sections, and the four developing containers **5051**, **5052**, **5053**, and **5054** can be rotated about a rotation shaft **5050a** while maintaining their relative positions. Every time the image formation corresponding to one page is finished, one of the developing devices is caused to selectively oppose the photoconductor **5020**, and the latent image formed on the photoconductor **5020** is successively developed using the toner T contained in the developing containers **5051**, **5052**, **5053**, and **5054**. It should be noted that each of these four developing containers **5051**, **5052**, **5053** and **5054** can be mounted and dismounted with respect to the printer main unit **5012**, which is an example of an image forming apparatus main unit, or more specifically, with respect to the holding sections **5055a**, **5055b**, **5055c** and **5055d** of the YMCK developing unit **5050**. When the developing containers **5051**, **5052**, **5053**, and **5054** are mounted to the holding sections **5055a**, **5055b**, **5055c**, and **5055d**, later-explained positioning pins **5592**, which are provided on the developing containers **5051**, **5052**, **5053** and **5054**, are provided on the printer main unit **5012**, and the developing containers **5051**, **5052**, **5053** and **5054** are positioned in the printer main unit **5012** by fitting these positioning pins **5592** into positioning pin fitting holes **5058** into which the positioning pins **5592** can be fitted (see FIG. 53). The details concerning YMCK developing unit **5050** and the developing units are explained later.

The primary image transfer unit **5060** is a device for transferring a single color toner image formed on the photoconductor **5020** to the intermediate image transfer member **5070**. When the four toner colors are successively transferred over one another, a full color toner image is formed on the intermediate image transfer member **5070**.

The intermediate image transfer member **5070** is a layered endless belt made by providing an aluminum vapor deposition layer on the surface of a PET film and forming a semiconductive coating on its surface. The intermediate image transfer member **5070** is driven to rotate at substantially the same circumferential speed as the photoconductor **5020**.

The secondary image transfer unit **5080** is a device for transferring the single-color toner image or the full-color toner image formed on the intermediate image transfer member **5070** onto a medium such as paper, film, and cloth.

The fixing unit **5090** is a device for fusing the single-color toner image or the full-color toner image, which has been transferred to the medium, onto the medium to turn it into a permanent image.

The cleaning unit **5075** is a device that is provided between the primary image transfer **5060** and the charging unit **30**, has a rubber cleaning blade **5076** coming into contact with the surface of the photoconductor **5020**, and is for removing the toner T remaining on the photoconductor **5020** by scraping it off with the cleaning blade **5076** after the toner image has been transferred onto the intermediate image transfer member **5070** by the primary image transfer unit **5060**.

110

The control unit **5100** is made of a main controller **5101** and a unit controller **5102**, as shown in FIG. 43. An image signal and a control signal are input into the main controller **5101**, and in accordance with a command based on the image signal and the control signal, the unit controller **5102** controls the various units and the like to form the image.

Next, the operation during the image formation of the printer **5010** configured as above is described.

First, when an image signal and a control signal from a host computer not shown in the drawings are input into the main controller **5101** of the printer **5010** via an interface (I/F) **5112**, the photoconductor **5020**, the developing roller, which is an example of a developer bearing roller, and the intermediate image transfer member **5070** are rotated under the control of the unit controller **5102** based on a command from the main controller **5101**. While rotating, the photoconductor **5020** is successively charged by the charging unit **5030** at a charging position.

The region of the photoconductor **5020** that has been charged is brought to an exposure position through rotation of the photoconductor **5020**, and a latent image corresponding to image information of a first color, for example yellow Y, is formed at that region by the exposing unit **5040**. The YMCK developing unit **5050** positions the yellow developing container **5054**, which contains yellow (Y) toner, at the developing position opposing the photoconductor **5020**.

The latent image formed on the photoconductor **5020** is brought to a developing position through the rotation of the photoconductor **5020**, and is developed with yellow toner by the yellow developing container **5054**. Thus, a yellow toner image is formed on the photoconductor **5020**.

The yellow toner image that is formed on the photoconductor **5020** is brought to the primary image transfer position through rotation of the photoconductor **5020** and is transferred to the intermediate image transfer member **5070** by the primary image transfer unit **5060**. At this time, a primary image transfer voltage, which has an opposite polarity to the polarity to which the toner T is charged, is applied to the primary image transfer unit **5060**. It should be noted that during this process, the photoconductor **5020** and the intermediate image transfer member **5070** are in contact, whereas the secondary image transfer unit **5080** is kept separated from the intermediate image transfer member **5070**.

By sequentially repeating the above-described processes with each of the developing containers for the second, the third, and the fourth color, toner images in four colors corresponding to the respective image signals are transferred to the intermediate image transfer member **5070** in a superimposed manner. Thus, a full color toner image is formed on the intermediate image transfer member **5070**.

With the rotation of the intermediate image transfer member **5070**, the full-color toner image formed on the intermediate image transfer member **5070** reaches a secondary image transfer position, and is transferred onto the medium by the secondary image transfer unit **5080**. It should be noted that the medium is carried from the paper supply tray **5092** to the secondary image transfer **5080** via the paper supply roller **5094** and the registration rollers **5096**. Also, when performing the image transfer operation, the secondary image transfer unit **5080** is pressed against the intermediate image transfer member **5070** while applying a secondary image transfer voltage to it.

The full-color toner image transferred onto the medium is heated and pressurized by the fixing unit **5090** and thus fused to the medium.

On the other hand, after the photoconductor **5020** has passed the primary image transfer position, the toner T adher-

ing to the surface of the photoconductor **5020** is scraped off by the cleaning blade **5076** that is supported by the cleaning unit **5075**, and the photoconductor **5020** is prepared for charging for the next latent image to be formed. The scraped-off toner T is collected into a remaining-toner collector of the cleaning unit **5075**.

====Overview of the Control Unit====

The configuration of the control unit **5100** is described next, with reference to FIG. 43. The main controller **5101** of the control unit **5100** is electrically connected to the host computer via an interface **5112**, and is provided with an image memory **5113** for storing image signals input into it from the host computer. The unit controller **5102** is electrically connected to each of the units (i.e., the charging unit **5030**, the exposing unit **5040**, the YMCK developing unit **5050**, the primary image transfer unit **5060**, the cleaning unit **5075**, the secondary image transfer unit **5080**, the fixing unit **5090** and the displaying unit **5095**), and it detects the state of the units by receiving signals from sensors provided in those units, and controls each of the units based on the signals that are input from the main controller **5101**.

Also, the CPU **5120** provided in the unit controller **5102** is electrically connected to a non-volatile storage element (hereinafter, also referred to as "main unit-side memory **5122**") such as an EEPROM via the serial interface (I/F) **5121**. Also, the CPU **5120** is capable of wirelessly communicating with elements **5051a**, **5052a**, **5053a**, and **5054a**, which are respectively provided in the developing containers **5051**, **5052**, **5053**, and **5054**, via the serial interface **5121**, a send-receive circuit **5123**, and a main unit-side antenna (antenna for element communication) **5124**, which is an example of an antenna. During the wireless communication, the main unit-side antenna **5124** writes information into the elements **5051a**, **5052a**, **5053a**, and **5054a** provided on the developing containers **5051**, **5052**, **5053**, and **5054**, respectively. The main unit-side antenna **5124** can also read information from the elements **5051a**, **5052a**, **5053a** and **5054a**.

Thus, the main unit-side memory **5122** and the elements **5051a**, **5052a**, **5053a** and **5054a** can communicate with each other. That is to say, the transfer of information stored in the main unit-side memory **5122** to the elements **5051a**, **5052a**, **5053a** and **5054a**, as well as the transfer of information stored in the **5051a**, **5052a**, **5053a** and **5054a** to the main unit-side memory **5122** can be accomplished.

====Configuration Example of the Developing Device====

A configuration example of the developing devices is explained next, using FIG. 44 to FIG. 55. FIG. 44 is a perspective view of a developing device. FIG. 45 is a cross-sectional view showing the main structural components of this developing unit. FIG. 46 is a perspective view showing an arrangement in which a toner supply roller **5550** is installed a housing **5540**. FIG. 47 is a perspective view showing an arrangement in which a developing roller **5510** is installed in a holder **5526**, which is shown in FIG. 48. FIG. 48 is a perspective view showing an arrangement in which an upper sealing member **5520** and a regulating blade **5560** are integrated in the holder **5526**. FIG. 49 is a perspective view of a side plate **5580**. FIG. 50 is a perspective view showing an arrangement in which the upper sealing member **5520**, the regulating blade **5560** and the developing roller **510** are integrated in an integrating member **5525**. FIG. 51 is a perspective view showing an arrangement in which the integrating member **5525** shown in FIG. 50 is installed in the housing **5540** shown in FIG. 46. FIG. 52 is a perspective reference view showing the arrangement in FIG. 51 when the side plate **5580** is removed from the integrating member **5525**. FIG. 53

is a perspective view showing an arrangement in which the yellow developing container **5054** is mounted to the holding section **5055d** of the YMCK developing unit **5050**. FIG. 54 is a plan transparent view showing the configuration of the element **5054a**. FIG. 55 is a block diagram illustrating the internal configuration of the element **5054a**.

It should be noted that the cross-sectional view shown in FIG. 45 shows a cross section of the developing device taken along a plane perpendicular to the longitudinal direction shown in FIG. 44. Moreover, in FIG. 45, like in FIG. 42, the vertical direction is indicated by arrows, and for example, the center axis of the developing roller **5510** is lower than the center axis of the photoconductor **5020**. Also, in FIG. 45, the yellow developing container **5054** is shown in a state positioned at a developing position that is in opposition to the photoconductor **5020**.

The black developing container **5051** containing black (K) toner, the magenta developing container **5052** containing magenta (M) toner, the cyan developing container **5053** containing cyan (C) toner, and the yellow developing container **5054** containing yellow (Y) toner are mounted to the YMCK developing unit **5050**. However, since the configuration of the developing containers is the same, only the yellow developing container **5054** will be explained below.

The yellow developing container **5054** includes the housing **5540**, the toner supply roller **5550**, the developing roller **5510**, the upper sealing member **5520**, the regulating blade **5560**, the integrating member **5525**, and the element **5054a**, for example.

The housing **5540** is manufactured by welding together a plurality of integrally-molded housing sections made of resin, that is, an upper housing section **5542** and a lower housing section **5543**. A toner containing member **5538** for containing toner T is formed inside the housing **5540**. The toner containing member **5538** is divided by a partitioning wall **5545** for partitioning the toner T, which protrudes inwards (in the vertical direction of FIG. 45) from the inner wall, into two toner containing sections, namely, a first toner containing section **5538a** and a second toner containing section **5538b**.

The first toner containing section **5538a** and the second toner containing section **5538b** are in communication at the top, and in the state shown in FIG. 45, the movement of toner T is restricted by the partitioning wall **5545**. However, when the YMCK developing unit **5050** rotates, the toner contained in the first toner containing section **5538a** and the second toner containing section **5538b** is temporarily collected on the side where the top sides are in communication in the developing position, and when it returns to the state shown in FIG. 45, the toner is mixed and returned to the first toner containing section **5538a** and the second toner containing section **5538b**. That is to say, by rotating the YMCK developing unit **5050**, the toner T in the developing containers is suitably stirred. Therefore, in the present embodiment, the toner containing member **5538** is not provided with a stirring member, but it is also possible to provide a stirring member for stirring the toner T contained in the toner containing member **5538**. Moreover, as shown in FIG. 45, the housing **5540** (that is, the first toner containing section **5538a**) has an opening **5572** at its lower side, and the developing roller **5510**, which is explained below, is arranged such that it protrudes into this opening **5572**. Moreover, a side wall **5544** positioned at one end in the longitudinal direction of the housing **5540** (the yellow developing container **5054**) is provided with a pin **5544a**, which can be fitted into a pin fitting hole **5588** (see FIG. 46) provided on the later-described integrating member **5525** (side plate **5580**).

As shown in FIG. 45 and FIG. 46, the toner supply roller 5550 is provided in the above-mentioned first toner accommodation section 5538a and not only supplies toner T that is contained in this first toner containing section 5538a to the later-described developing roller 5510, but also scrapes off, from the developing roller 5510, toner T that has remained on the developing roller 5510 after developing. The toner supply roller 5550 is made of polyurethane foam, for example, and is in contact with the developing roller 5510 in a state of elastic deformation. The toner supply roller 5550 is disposed at a lower part of the first toner containing section 5538a, and the toner T contained in the first toner containing section 5538a is supplied to the developing roller 5510 by the toner supply roller 5550 at the lower part of the first toner containing section 5538a. As shown in FIG. 46, a shaft of the toner supply roller 5550 is supported rotatably by the housing 5540 with two supply roller bearings 5578, namely a supply roller bearing 5578a positioned at one end in the longitudinal direction of the toner supply roller 5550 (yellow developing container 5054) and a supply roller bearing 5578b positioned at the other end in the longitudinal direction. More specifically, the housing 5540 is provided with, as supply roller fitting holes 5546 into which the supply roller bearings 5578 can be fitted, a supply roller fitting hole 5546a on one end into which the supply roller bearing 5578a on the one end can be fitted and a supply roller fitting hole 5546b on the other end into which the supply roller bearing 5578b on the other end can be fitted. The toner supply roller 5550 is supported rotatably by the housing 5540 with the supply roller bearing 5578a on the one end, which is fitted into the supply roller fitting hole 5546a on the one end and the supply roller bearing 5578b on the other end, which is fitted into the supply roller fitting hole 5546b on the other end. As shown in FIG. 45, the toner supply roller 5550 rotates in a direction (the clockwise direction in FIG. 45) that is opposite to the rotation direction of the developing roller 5510 (the counterclockwise direction in FIG. 45). Its center axis is lower than the rotation center axis of the developing roller 5510. It should be noted that a supply roller driving gear wheel 5610 for driving the toner supply roller 5550 is provided at the end (one end in axial direction) of the toner supply roller 5550 (see FIG. 44).

The developing roller 5510 bears toner T and carries it to the developing position opposite the photoconductor 5020. This developing roller 5510 is fabricated from an aluminum alloy, such as 5056 aluminum alloy or 6063 aluminum alloy, or an iron alloy such as STKM, and may be nickel-plated or chromium-plated if necessary.

The developing roller 5510 extends along the longitudinal direction of the yellow developing container 5054 and includes a shaft 5510a and a large-diameter section 5510b. The shaft 5510a is supported by a later-described holder 5526 through two developing roller bearings 5576, namely a developing roller bearing 5576a on one end that is positioned on one end in the longitudinal direction of the developing roller 5510 (the yellow developing container 5054) and a developing roller bearing 5576b on the other end that is positioned on the other end in the longitudinal direction, thereby rotatably supporting the developing roller 5510. As shown in FIG. 45, the developing roller 5510 rotates in a direction (the counterclockwise direction in FIG. 45) that is opposite to the rotation direction of the photoconductor 5020 (the clockwise direction in FIG. 45). Its center axis is lower than the center axis of the photoconductor 5020. It should be noted that a developing roller driving gear wheel 56512, which is an example of a first driving wheel, for driving the developing roller 5510 is provided at one end of the developing roller 5510 (see FIG. 44).

Moreover, in the state in which the yellow developing container 5054 opposes the photoconductor 5020, there is a gap between the developing roller 5510 and the photoconductor 5020. That is to say, the yellow developing container 5054 develops the latent image formed on the photoconductor 5020 in a noncontacting manner. It should be noted that during the development of the latent image formed on the photoconductor 5020, an alternating electric field is formed between the developing roller 5510 and the photoconductor 5020.

The upper sealing member 5520, which abuts against the developing roller 5510 along its axial direction, allows the movement of toner T that has remained on the developing roller 5510 after passing the developing position and restricts the movement of toner T inside the housing 5540 out of the housing 5540. This upper sealing member 5520 is a seal made of polyethylene film or the like. The upper sealing member 5520 is supported by an upper seal support section 5527 of the holder 5526, which is described later, and is disposed such that its longitudinal direction extends in the axial direction of the developing roller 5510 (see FIG. 48). The contact position where the upper sealing member 5520 contacts the developing roller 5510 is above the center axis of the developing roller 5510.

Moreover, as shown in FIG. 45, an upper seal biasing member 5524 made of an elastic member such as Moltopren is provided in a compressed state between the upper seal support section 5527 and the surface of the upper sealing member 5520 that is on the opposite side of the contact surface 5520b contacting the developing roller 5510 (this surface is also referred to as opposite surface 5520c). This upper seal biasing member 5524 presses the upper sealing member 5520 against the developing roller 5510 by biasing the upper sealing member 5520 towards the developing roller 5510 with its biasing force.

The regulating blade 5560 abuts against the developing roller 5510 along its axial direction, and regulates the thickness of the toner T borne by the developing roller 5510. Moreover, it applies a charge to the toner T borne by the developing roller 5510. The regulating blade 5560 includes a rubber part 5560a and a rubber supporting part 5560b. The rubber part 5560a is made of silicone rubber or urethane rubber, for example, and the rubber supporting part 5560b is a thin plate of phosphor bronze or stainless steel, for example, having elasticity.

The rubber part 5560a is supported by the rubber supporting part 5560b, and the rubber supporting part 5560b presses the rubber part 5560a against the developing roller 5510 with its biasing force. With one end of the rubber supporting part 5560b being supported by a regulating blade support part 5528 of the holder 5526, which is described later, the rubber supporting part 5560b is attached to the regulating blade support part 5528.

The end of the regulating blade 5560 on the side opposite the side supported by the regulating blade support part 5528, that is, its front end, is not in contact with the developing roller 5510, and a portion thereof that is removed from this front end by a predetermined distance is in contact with the developing roller 5510 over a certain width. That is to say, the regulating blade 5560 does not come into contact with the developing roller 5510 at its edge but rather at a mid section thereof. Also, the regulating blade 5560 is disposed such that its front end is facing upstream with respect to the direction in which the developing roller 5510 rotates, and is in so-called counter contact. It should be noted that the contact position where the regulating blade 5560 contacts the developing

115

roller 5510 is below the center axis of the developing roller 5510 and is below the center axis of the toner supply roller 5550.

Moreover, end seals 5574 (see FIG. 48) are provided on the outer side in longitudinal direction of the rubber part 5560a of the regulating blade 5560. These end seals 5574, which are made of non-woven fabric, abut along the circumferential direction of the developing roller 5510 against the ends in axial direction of the developing roller 5510 and have the function of preventing the leaking of toner T from between its circumferential surface and the housing 5540.

The integrating member 5525 is a member for integrating the various members, such as the developing roller 5510 or the driving gear wheels. It is mainly made of two members, namely the holder 5526 and the side plate 5580, which is positioned at one end in longitudinal direction of the holder 5526 (the yellow developing container 5054) and is an example of a metal plate (see FIG. 50).

The holder 5526 is a member made of metal. As shown in FIG. 48, it includes the upper seal support section 5527 extending along its longitudinal direction (that is, in the axial direction of the developing roller 5510), the regulating blade supporting part 5528 also extending in its longitudinal direction (that is, in the axial direction of the developing roller 5510), and developing roller supporting sections 5529, which are provided on the outer side, with respect to the longitudinal direction (the axial direction), of the upper seal support section 5527 and the regulating blade supporting part 5528 and intersects with the longitudinal direction (the axial direction).

The developing roller support sections 5529 include a developing roller support section 5529a positioned on one end in the longitudinal direction of the holder 5526 (the yellow developing container 5054) and a developing roller support section 5529b positioned on the other end in the longitudinal direction of the holder 5526 (the yellow developing container 5054). Furthermore, the developing roller support section 5529a on the one end and the developing roller support section 5529b on the other end include, as developing roller fitting holes 5530 into which the developing roller bearings 5576 can be fitted, a developing roller fitting hole 5530a on one end, into which the developing roller bearing 5576a on the one end can be fitted, and a developing roller fitting hole 5530b on the other end, into which the developing roller bearing 5576b on the other end can be fitted. Thus, the developing roller 5510 can be rotatably supported by the holder 5526 with the developing roller bearing 5576a on the one end, which is fitted into the developing roller fitting hole 5530a on the one end, and the developing roller bearing 5576b on the other end, which is fitted into the developing roller fitting hole 5530b on the other end (see FIG. 47). It should be noted that the developing roller support section 5529a on the one end is provided with an intermediate gear wheel support section 5531 for rotatably supporting a later-described intermediate gear wheel 5614.

Moreover, the upper sealing member 5520 is supported at an end 5520a in shorter direction (see FIG. 45) by the upper seal support section 5527, and the regulating blade 5560 is supported at an end 5560c in shorter direction (see FIG. 45) by the regulating blade support part 5528. Furthermore, as shown in FIG. 48, the regulating blade 5560 is supported at its ends 5560d in longer direction by the end seals 5574.

The side plate 5580 is a member made of metal and, as shown in FIG. 49, includes a support section fitting hole 5582 into which the intermediate gearwheel support section 5531 can be fitted, a developing roller fitting hole 5584 into which the developing roller bearing 5576a on the one end can be fitted, a supply roller fitting hole 5586 into which the supply

116

roller bearing 5578a on the one end can be fitted, a pin fitting hole 5588 into which the pin 5544a can be fitted, a developing device-side gear wheel support section 5590 for rotatably supporting a later-described developing device-side gear wheel 5616, which is an example of a second driving wheel, and a positioning pin 5592 for positioning the yellow developing container 5054 in the printer main unit 5012.

As shown in FIG. 50, the integrating member 5525 is constituted by fitting the intermediate gear wheel support section 5531 and the one-end developing roller bearing 5576a of the holder 5526 in which the developing roller 5510 is installed respectively into the support section fitting hole 5582 and the developing roller hole 5584 of the side plate 5580.

As shown in FIG. 51 and FIG. 52, the thusly constituted integrating member 5525 is installed in the housing 5540, which is provided with the toner supply roller 5550, as shown in FIG. 46, via a housing seal 5602 (see FIG. 45) for preventing the leakage of toner T from between the integrating member 5525 and the housing 5540. During this, the supply roller bearing 5578a on the one end and the pin 5544a provided on the housing 5540 including the toner supply roller 5550 are respectively fitted into the supply roller fitting hole 5586 and the pin fitting hole 5588 of the integrating member 5525 at the one end in longitudinal direction of the yellow developing container 5054. Consequently, the toner supply roller 5550 is rotatively supported by the supply roller hole 5586 of the integrating member 5525 and the supply roller hole 5546 of the housing 5540 mentioned above.

In the foregoing, it was explained that the developing roller driving gear wheel 5612 and the supply roller driving gear wheel 5610 are respectively provided at the end (the end in axial direction) of the developing roller 5510 and the toner supply roller 5550, but as shown in FIG. 44, the yellow developing container 5054 also includes a developing device-side gear wheel 5616 and an intermediate gear wheel 5614 besides these gear wheels.

The developing device-side gear wheel 5616 is a gear wheel for receiving driving force from the printer main unit 5012, or more specifically from a later-described main unit-side gear wheel 5056, and transmitting this driving force to the developing roller driving gear wheel 5612 and the supply roller driving gear wheel 5610 in a state in which the yellow developing container 5054 is mounted to the printer main unit 5012. This developing device-side gear wheel 5616 is supported rotatively by the above-mentioned developing device-side gear wheel support section 5590.

The intermediate gear wheel 5614 is a gear wheel serving as a medium when the developing device-side gearwheel 5616 transmits driving force to the developing roller driving gear wheel 5612 and the supply roller driving gear wheel 5610. That is to say, when the yellow developing container 5054 is mounted to the printer main unit 5012, the developing device-side gear wheel 5616 receives driving force from the printer main unit 5012 and transmits the driving force via the intermediate gear wheel 5614 to the developing roller driving gear wheel 5612 and the supply roller driving gear wheel 5610. This intermediate gear wheel 5614 is supported rotatively by the above-mentioned intermediate gear wheel support section 5531.

As shown in FIG. 44, the developing device-side gear wheel 5616 meshes with the intermediate gear wheel 5614, the intermediate gear wheel 5614 meshes with the developing roller driving gear wheel 5612, and the developing roller driving gear wheel 5612 meshes with the supply roller driving gear wheel 5610. Moreover, as shown in FIG. 53, the devel-

oping device-side gear wheel 5616 meshes with the main unit-side gear wheel 5056 with which the printer main unit 5012 is provided.

This main unit-side gear wheel 5056 applies the driving force received from a developing device driving motor 5057 (see FIG. 58), which is as an example of a motor, to the developing device-side gear wheel 5616. Then, the developing device-side gear wheel 5616 transmits the driving force received from the main unit-side gear wheel 5056 via the intermediate gear wheel 5614 to the developing roller driving gear wheel 5612. Due to the meshing of the developing roller driving gear wheel 5612 with the supply roller driving gear wheel 5610, the driving force transmitted to the developing roller driving gear wheel 5612 is also transmitted to the supply roller driving gear wheel 5610.

As noted above, the element 5054a is a member that can communicate wirelessly with the main unit-side antenna 5124. This element 5054a has an adhesive surface on its rear side and is adhered to an indented section provided in the housing 5540. As shown in FIG. 44 for example, the position where the element 5054a is adhered is at an end in the longitudinal direction of the yellow developing container 5054, namely at the end on the side where the aforementioned developing roller driving gear wheel 5612 is positioned.

As shown in FIG. 54, the element 5054a has a non-contact IC chip 5054b, a resonance capacitor 5054c that is formed by etching a metal film, and a flat coil serving as an antenna 5054d. These are mounted onto a plastic film and covered by a transparent coversheet. As shown in FIG. 55, the non-contact IC chip 5054b includes a rectifier 5054e, a signal analysis section RF (Radio Frequency) 5054f, a controller 5054g, and the memory cell 5054h. The memory cell 5054h is a nonvolatile memory that can be electrically read and written, such as an NAND flash ROM, and is capable of storing information that has been written in it and reading that stored information from the outside.

The antenna 5054d of the element 5054a and the main unit-side antenna 5124 communicate wirelessly with one another, so that information stored in the memory cell 5054h can be read and information can be written to the memory cell 5054h. Also, the high-frequency signals that are generated by the send-receive circuit 5123 of the printer main unit 5012 are induced as a high-frequency magnetic field via the main unit-side antenna 5124. This high-frequency magnetic field is absorbed via the antenna 5054d of the element 5054a and is rectified by the rectifier 5054e, thus serving as a DC power source for driving the circuits in the non-contact IC chip 5054b.

The following is an explanation of the operation of the thusly configured yellow developing container 5054 during developing. The toner supply roller 5550 supplies, through its rotation, toner T contained in the toner containing member 5538 to the developing roller 5510. In this situation, the toner supply roller 5550 is driven by the driving force transmitted to it by the supply roller driving gear wheel 5610, and rotates. As the developing roller 5510 rotates, the toner T that is supplied to the developing roller 5510 is brought to the contact position of the regulating blade 5560, and when it passes the contact position, the layer thickness of the toner T is regulated, and a charge is applied to it. The toner T on the developing roller 5510, whose layer thickness has been regulated and which has been charged, is brought to the developing position in opposition to the photoconductor 5020 by further rotation of the developing roller 5510, and is supplied for the development of the latent image formed on the photoconductor 5020 in an alternating electric field at the developing position. The toner T on the developing roller 5510 that has passed the

developing position due to further rotation of the developing roller 5510 passes the upper sealing member 5520 and is collected in the developing device without being scraped off by the upper sealing member 5520. It should be noted that the developing roller 5510 is driven by the driving force transmitted to it by the developing roller driving gear wheel 5612, and rotates. Moreover, the toner T that still remains on the developing roller 5510 is stripped off by the toner supply roller 5550.

10 <<<About the Positioning of the Gear Wheels>>>

In order to suitably drive the developing roller 5510, the above-mentioned developing device-side gear wheel 5616 and the developing roller driving gear wheel 5612 need to be positioned with high precision. In developing devices in which the developing device-side gear wheel 5616 and the developing roller driving gear wheel 5612 are not positioned with high precision, an improper developing operation will be performed, since the developing roller 5510 is not driven properly. Similarly, if the developing device is provided with a toner supply roller 5550, then it is necessary to position the supply roller driving gear wheel 5610 with high precision, in order to suitably drive the toner supply roller 5550. Furthermore, if the developing device is provided with an intermediate gear wheel 5614, then also this intermediate gear wheel 5614 needs to be positioned with high precision.

The following is an explanation of how these gear wheels are positioned in the yellow developing container 5054 according to this embodiment. As noted above, the intermediate gear wheel support section 5531 and the bearing 5576a for the developing roller at the one end of the holder 5526 in which for example the developing roller 5510 is installed are fitted respectively into the support section fitting hole 5582 and the developing roller fitting hole 55B4 of the side plate 5580. Thus, the relative position of the side plate 5580 and the holder 5526 in which the developing roller 5510 is installed is positioned.

Also, the bearing 5578a for the supply roller at the one end is fitted into the supply roller fitting hole 5586 of the side plate 5580. And moreover, the side plate 5580 is provided with the developing device-side gear wheel support section 5590 for rotatively supporting the developing device-side gear wheel 5616, and the holder 5526 is provided with the intermediate gear wheel support section 5531 for rotatively supporting the intermediate gear wheel 5614. Thus, the relative positions of the developing device-side gear wheel support section 5590, the intermediate gear wheel support section 5531, the bearing 5576a for the developing roller on the one side and the bearing 5578a for the supply roller on the one side are positioned.

Furthermore, the developing device-side gearwheel 5616 is supported by the developing device-side gear wheel support section 5590, and the intermediate gear wheel 5614 is supported by the intermediate gear wheel support section 5531. The developing roller driving gear wheel 5612 and the support roller driving gear wheel 5610 are respectively provided at ends (ends in axial direction) of the developing roller 5510 and the toner supply roller 5550. Thus, the relative positions of the developing device-side gear wheel 5616, the intermediate gear wheel 5614, the developing roller driving gear wheel 5612 and the supply roller driving gear wheel 5610 are positioned.

Thus, by cooperating with the holder 5526, the side plate 5580 has the function of serving as a positioning member for positioning the above-noted gear wheels (the developing device-side gear wheel 5616, the developing roller driving gear wheel 5612, the intermediate gear wheel 5614, and the supply roller driving gear wheel 5610).

==Overview of the YMCK Developing Unit==

Next, an overview of the YMCK developing unit **5050** is given using FIG. 56A, FIG. 56B and FIG. 56C. The YMCK developing unit **5050** includes a central shaft **5050a** positioned in its center. A support frame **5055** for holding the developing devices is fixed to this central shaft **5050a**. The central shaft **5050a** spans the distance between two frame side plates (not shown in the drawings) of the housing of the printer **5010**, which support its two end portions. It should be noted that the axial direction of the central shaft **5050a** intersects with the vertical direction.

This support frame **5055** includes four holding sections **5055a**, **5055b**, **5055c**, and **5055d**, in which the four developing devices **5051**, **5052**, **5053**, and **5054** are removably held, arranged at spacings of 90° in circumferential direction.

A pulse motor not shown in the drawings is connected via a clutch to the central shaft **5050a**, and by driving this pulse motor, the support frame **5055** is rotated and the four developing devices **5051**, **5052**, **5053** and **5054** can be positioned at predetermined positions.

FIG. 56A, FIG. 56B, and FIG. 56C illustrate the three stop positions of the rotating YMCK developing units **5050**. FIG. 56A shows the home position (referred to as "HP position" below), which is the stand-by position when waiting for the execution of image formation, and is also the stop position serving as a reference position for the rotational direction of the YMCK developing unit **5050**. FIG. 56B shows the communication position of the yellow developing device **5054** mounted to the YMCK developing unit **5050**. FIG. 56C shows the mounting and dismounting position of the yellow developing device **5054**.

Here, in FIG. 56B and FIG. 56C, the communication position and the mounting and dismounting position of the yellow developing device **5054** are shown, but the communication position and the mounting and dismounting position of any developing device can be achieved by rotating the YMCK developing unit **5050** successively by amounts of 90°.

First, the HP position shown in FIG. 56A is explained. A HP detection section (not shown in the drawings) for detecting the HP position is provided at one end of the central shaft **5050a** of the YMCK developing unit **5050**. This HP detection section includes a circular disk for generating a signal that is attached to one end of the central shaft **5050a**, and an HP sensor made of a photo-interrupter including a light-emitting section and a light-receiving section. The outer edge of the circular disk is arranged such that it is positioned between the light-emitting section and the light-receiving section of the HP sensor. When slit sections formed in the circular disk are moved to a detection position of the HP sensor, the signal that is output by the HP sensor changes from "L" to "H". Then, the HP position of the YMCK developing unit **5050** is detected from this change in signal level and the pulse number of the pulse motor, and taking this HP position as a reference, it is possible to position the developing devices at the communication position or the like.

FIG. 56B shows the communication position of the yellow developing device **5054**, after letting the pulse motor rotate by a predetermined number of pulses from the HP position. In the communication position of the yellow developing roller **5054** shown in FIG. 56B, the element **5054a** of the yellow developing device **5054** communicates wirelessly with the main unit-side antenna **5124** with which the printer main unit **5012** is provided. It should be noted that the communication position for the yellow developing device **5054** is the developing position of the black developing device **5051**, in which the developing roller **510** of the black developing device **5051** and the photoconductor **5020** face each other. That is to say,

the communication position of the YMCK developing unit **5050** for the yellow developing device **5054** is the developing position of the YMCK developing unit **5050** for the black developing device **5051**. Moreover, when the pulse motor rotates the YMCK developing unit **5050** for 90° in the counterclockwise direction, the communication position of the black developing device **5051** and the developing position of the cyan developing device **5053** are attained. When the YMCK developing unit **5050** is rotated by amounts of 90° each, the communication position and the developing position of each of the developing units are successively attained.

It should be noted that the positional relation between the element **5054a** and the main unit-side antenna **5124** in the communication position is explained in detail later.

Moreover, one of the two frame side plates that support the YMCK developing unit **5050** and are part of the housing of the printer **5010** is provided with an opening **5037** reserved for mounting and dismounting through which one developing device can be passed. This opening **5037** reserved for mounting and dismounting is formed at such a position that, when the YMCK developing unit **5050** is rotated and stopped at one of the mounting and dismounting positions that are set for each of the developing devices, only the corresponding developing device (here, the yellow developing device **5054**) can be removed by pulling it out in a direction parallel to the central shaft **5050a**, as shown in FIG. 56C. Moreover, the opening **5037** reserved for mounting and dismounting is formed slightly larger than the outer shape of the developing device, and in the mounting and dismounting position, not only can the developing device be retrieved, but a new developing device can be inserted in the direction parallel to the central shaft **5050a** through this opening **5037** reserved for mounting and dismounting, and the developing device can be mounted to the support frame **5055**. While the YMCK developing unit **5050** is not positioned in a mounting and dismounting position, the mounting and dismounting of developing devices is prevented by the frame side plates.

It should be noted that the YMCK developing unit **5050** is provided with a locking mechanism not shown in the drawings, in order to position and fix the YMCK developing unit **5050** reliably at the above-noted positions.

==About the Positional Relation Between Element, Main Unit-Side Antenna and Members in their Vicinity==

As noted above, in the communication positions of the developing devices, which are stop positions of the YMCK developing unit **5050**, the elements of the developing devices communicate wirelessly with the main unit-side antenna **5124** with which the printer main unit **5012** is provided. Referring to FIG. 57 and FIG. 58, the following is an explanation of the positional relation between the element and the main unit-side antenna **5124**, when one of the elements performs wireless communication with the main unit-side antenna **5124**. FIG. 57 is a diagrammatic view showing the positional relation between the element **5054a** and the main unit-side antenna **5124** when the element **5054a** communicates wirelessly with the main unit-side antenna **5124**. FIG. 58 is a diagrammatic view showing the position of the developing device driving motor **5057**.

It should be noted that as the communication positions of the developing device, there are the communication position of the black developing device **5051**, the communication position of the magenta developing device **5052**, the communication position of the cyan developing device **5053**, and the communication position of the yellow developing device **5054**, but the positional relation between the element and the main unit-side antenna **5124** is the same for all these commu-

121

nication positions, so that in the following, the positional relationship between the element **5054a** of the yellow developing device **5054** and the main unit-side antenna **5124** is explained. Moreover, in the following, not only the positional relationship between the element **5054a** and the main unit-side antenna **5124**, but also the positional relationship between these and members in their vicinity is considered.

As shown in FIG. 57, in the communication position of the yellow developing device **5054**, the element **5054a** is in a state facing the main unit-side antenna **5124** across a gap **5150**, such that the element **5054a** of the yellow developing device **5054** can perform suitable wireless communication with the main unit-side antenna **5124** with which the printer main unit **5012** is provided. That is to say, when the yellow developing device **5054** is mounted to the holding section **5055d**, it rotates together with the rotation of the YMCK developing unit **5050**, so that when the element **5054a** of the yellow developing device **5054** faces the main unit-side antenna **5124** across the gap **5150**, the element **5054a** performs wireless communication with the main unit-side antenna **5124**. It should be noted that the distance **d** between the element **5054a** and the main unit-side antenna **5124** when the element **5054a** faces the main unit-side antenna **5124** (in other words, the width **d** of the gap **5150**) is about 8 mm.

Moreover, as noted above, the yellow developing device **5054** is provided with a side plate **5580** made of metal. And as shown in FIG. 51 and FIG. 57, when the element **5054a** performs wireless communication with the main unit-side antenna **5124**, a portion of this side plate **5580** (in this embodiment, the upper portion **5580a**) is positioned at a position corresponding to this gap **5150** (this corresponding position is denoted as **P1** in FIG. 57), to the outer side of the gap **5150** and extending along the direction from the element **5054a** toward the main unit-side antenna **5124** (this direction is denoted as **X** in FIG. 57).

Moreover, as shown in FIG. 57, the printer main unit **5012** is provided with a plate made of metal (this plate is referred to as the main unit-side metal plate **5126**), surrounding the main unit-side antenna **5124**. When the element **5054a** performs wireless communication with the main unit-side antenna **5124**, also a portion of this main unit-side metal plate **5126** (in the present embodiment, the bottom portion **5126a**) is positioned at the position **P1** corresponding to the gap **5150** to the outer side of the gap **5150** and extending along the direction **X** from the element **5054a** toward the main unit-side antenna **5124**.

The upper portion **5580a** of the side plate **5580** and the lower portion **5126a** of the main unit-side metal plate **5126** respectively fulfill the role of decreasing the amount of noise that intrudes into the gap **5150** between the element **5054a** and the main unit-side antenna **5124**.

That is to say, as explained in the section stating the problem to be solved by the invention, when the element **5054a** performs wireless communication with the main unit-side antenna **5124**, electromagnetic waves are propagated into the gap **5150** between the element **5054a** and the main unit-side antenna **5124**. Therefore, when too much noise intrudes into this gap **5150** from the outside, suitable wireless communication is obstructed. In the present embodiment, when the element **5054a** communicates wirelessly with the main unit-side antenna **5124**, (the upper portion **5580a** of) the side plate **5580** and (the lower portion **5126a**) of the main unit-side metal plate **5126**, which are both made of metal, are positioned at the position **P1** corresponding to the gap **5150** to the outer side of the gap **5150** and extending along the direction **X** from the element **5054a** toward the main unit-side antenna **5124** so that they suitably block the intrusion of noise from

122

the outside into the gap **5150**. Consequently, the amount of noise intruding into the gap **5150** is suitably decreased, and suitable wireless communication can be performed.

Moreover, in the present embodiment, when the element **5054a** communicates wirelessly with the main unit-side antenna **5124**, the side plate **5580** is positioned between the developing device driving motor **5057** and the gap **5150**. That is to say, the developing device driving motor **5057** is provided at the position marked by the black frame in FIG. 58, on the opposite side of the element **5054a** when seen from the side plate **5580** (the yellow developing device **5054** is provided on the printer main unit **5012** such that the element **5054a** and the side plate **5580**, which are positioned at one end in longitudinal direction, are arranged behind the paper plane of FIG. 58, and the developing device driving motor **5057** is arranged even further behind the paper plane than the yellow developing device **5054**). Therefore, the yellow developing device **5054** rotates together with the rotation of the YMCK developing unit **5050** when it is mounted to the holding section **5055d**, and when the element **5054a** faces the main unit-side antenna **5124** across the gap **5150**, the side plate **5580** is positioned between the developing device driving motor **5057** and the gap **5150**.

And, since the developing device driving motor **5057** is a source of noise, in the present embodiment, the above-noted effect of the side plate **5580**, that is, the effect that the amount of noise intruding the gap **5150** is appropriately reduced, can be displayed even more effectively.

Other Embodiments

A developing device or the like according to the present invention was explained by way of the foregoing embodiment, but the foregoing embodiment of the invention is merely for the purpose of elucidating the present invention and is not to be interpreted as limiting the present invention. The invention can of course be altered and improved without departing from the gist thereof and equivalents are intended to be embraced therein.

In the foregoing embodiment, an intermediate image transfer type full-color laser beam printer was described as an example of the image forming apparatus, but the present invention can also be applied to various other types of image forming apparatuses, such as full-color laser beam printers that are not of the intermediate image transfer type, monochrome laser beam printers, copying machines, and facsimiles.

Moreover, also the photoconductor is not limited to a so-called photoconductive roller, which is configured by providing a photoconductive layer on the outer circumferential surface of a hollow cylindrical conductive base, and can also be a so-called photoconductive belt, which is configured by providing a photoconductive layer on the surface of a belt-shaped conductive base.

Moreover, in the present embodiment, when the developing devices are mounted to the holding sections **5055a**, **5055b**, **5055c** and **5055d**, they rotate together with the rotation of the YMCK developing unit **5050**, so that the elements communicate wirelessly with the main unit-side antenna **5124** when the elements with which the developing devices are provided face the main unit-side antenna **5124** across the gap **5150**. However, there is no limitation to this. For example, it is also possible that when the developing devices are mounted to the holding sections **5055a**, **5055b**, **5055c**, and **5055d**, without rotating the developing devices, the elements with which the developing devices are provided constantly face the main unit-side antenna **5124** across the gap **5150**.

Moreover, in the foregoing embodiment, the metal plate (side plate 5580) of the developing device is a positioning member for positioning the developing roller driving gear wheel 5612 and the developing device-side gear wheel 5616, but there is no limitation to this. That is to say, the metal plate of the developing device has the two functions of decreasing the amount of noise that intrudes into the gap 5150 to the main unit-side antenna 5124 and the function of serving as the positioning member, but there is no limitation to this, and it is also possible that it does not have the function of serving as the positioning member. However, with respect to one member having a plurality of functions, the foregoing embodiment is more effective.

Moreover, in the foregoing embodiment, the element is provided at the end in longitudinal direction of the developing device on the side where the developing roller driving gear wheel 5612 is positioned, but there is no limitation to this. For example, it is also possible that the element is provided in the middle in longitudinal direction of the developing device.

If the element is provided at the end in longitudinal direction of the developing device on the side where the developing roller driving gear wheel 5612 is positioned, then the element is positioned at a position that is closer to the side plate 5580, so that the side plate 5580 can more suitably decrease the amount of noise intruding into the gap 5150. For this reason, the foregoing embodiment is more preferable.

Moreover, in the foregoing embodiment, when the element communicates wirelessly with the main unit-side antenna 5124, the side plate 5580 is positioned between the motor and the gap 5150, but there is no limitation to this, and it is also possible that the side plate 5580 is not positioned between the motor and the gap 5150. Moreover, in the foregoing embodiment, the developing device driving motor 5057 is given as an example of that motor, but there is no limitation to this, and any motor may used. For example, the side plate 5580 may be positioned between the YMCK developing unit driving unit motor and the gap 5150, or the side plate 5580 may be positioned between the medium carry motor and the gap 5150. Moreover, in the foregoing embodiment, the printer main unit 5012 includes a main unit-side metal plate 5126 at least a portion of which is positioned at a position corresponding to the gap 5150 to the outer side of the gap 5150 and extending along the direction from the element toward the main unit-side antenna 5124 when the element communicates wirelessly with the main unit-side antenna 5124, but there is no limitation to this, and it is also possible that the printer main unit 5012 does not include this main unit-side metal plate 5126.

However, with regard to the fact that the amount of noise that intrudes into the gap between the element and the main unit-side antenna 5124 is decreased more suitably when the element communicates wirelessly with the main unit-side antenna 5124, the foregoing embodiment is preferable.

Moreover, in the foregoing embodiment, the metal plate of the developing device is provided further to the outside than the element in the longitudinal direction of the developing device, but there is no limitation to this. That is to say, it is not necessarily required that the metal plate of the developing device is provided at the region A1 in FIG. 59, and it may also be provided at the region S1, the region C1 or the region D1. It can also be provided at a plurality of the regions A1 to D1. It should be noted that FIG. 59 is a diagrammatic view showing the element of FIG. 44 from above, and is a diagram illustrating variations of the positions where the metal plate can be placed.

Moreover, in the foregoing embodiment, when the element 5054a communicates wirelessly with the main unit-side

antenna 5124, a portion of the side plate 5580 is positioned at a position P1 corresponding to the gap 5150 to the outer side of the gap 5150 and extending along the direction X from the element 5054a toward the main unit-side antenna 5124, but there is no limitation to this and it is also possible that, for example, all portions of the side plate 5580 are positioned at the position P1 corresponding to the gap 5150 to the outer side of the gap 5150 and extending along the direction X.

Similarly, in the foregoing embodiment, when the element 5054a communicates wirelessly with the main unit-side antenna 5124, a portion of the main unit-side metal plate 5126 is positioned at a position P1 corresponding to the gap 5150 to the outer side of the gap 5150 and extending along the direction X from the element 5054a toward the main unit-side antenna 5124, but there is no limitation to this and it is also possible that, for example, all portions of the main unit-side metal plate 5126 are positioned at the position P1 corresponding to the gap 5150 to the outer side of the gap 5150 and extending along the direction X.

20 ==Configuration of the Image Forming System Etc.==

Next, an embodiment of an image forming system serving as an example of an embodiment of the present invention is described with reference to the drawings.

FIG. 60 is an explanatory diagram showing the external configuration of an image forming system. An image forming system 5700 is provided with a computer 5702, a display device 5704, a printer 5706, input devices 5708, and reading devices 5710. In this embodiment, the computer 5702 is contained within a mini-tower type housing, but there is no limitation to this. A CRT (cathode ray tube), plasma display, or liquid crystal display device, for example, is generally used as the display device 5704, but there is no limitation to this. As the printer 5706, the printer described above is used. In this embodiment, the input devices 5708 are a keyboard 5708A and a mouse 5708B, but there is no limitation to these. In this embodiment, a flexible disk drive device 5710A and a CD-ROM drive device 5710B are used as the reading devices 5710, but the reading devices 5710 are not limited to these, and may also include an MO (magnetooptical) disk drive device or a DVD (digital versatile disk), for example.

FIG. 61 is a block diagram showing the configuration of the image forming system shown in FIG. 60. An internal memory 5802 such as a RAM is provided within the housing containing the computer 5702, and furthermore an external memory 45 such as a hard disk drive unit 5804 is provided.

In the above explanations, an example was given in which the image forming system is constituted by connecting the printer 5706 to the computer 5702, the display device 5704, the input devices 5708, and the reading devices 5710, but there is no limitation to this. For example, the image forming system may also be made of the computer 5702 and the printer 5706, and the image forming system does not have to be provided with any one of the display device 5704, the input devices 5708, and the reading devices 5710.

It is also possible that the printer 5706 has some of the functions or mechanisms of the computer 5702, the display device 5704, the input devices 5708, and the reading devices 5710. For example, the printer 5706 may be configured so as to have an image processing section for carrying out image processing, a display section for carrying out various types of displays, and a recording media mounting and dismounting section into and from which recording media storing image data captured by a digital camera or the like are inserted and taken out.

As an overall system, the image forming system that is thus achieved is superior to conventional systems.

Overview of Image Forming Apparatus of Seventh Embodiment

Referring to FIGS. 62 to 67, an overview of a laser beam printer (hereinafter, also referred to as "printer") 6010 serving as an example of an image forming apparatus is described. FIG. 62 is a diagram illustrating the configuration of a printer main unit 6010a to which developing containers 6051, 6052, 6053 and 6054 can be mounted and dismounted. FIG. 63 is a diagram showing the main structural components constituting the printer 6010. FIG. 64 is a block diagram showing the control unit 6100 of the printer 6010. FIG. 65 is a perspective view of a developing container holding unit 6050. FIG. 66 is a diagram showing the developing container holding unit 6050 in a state in which a yellow developing container 6054 is mounted to a mounting and dismounting section 6050d. FIG. 67 is a diagram showing the positions of the mounted developing container and the developing container holding unit. It should be noted that FIG. 63 is a diagram of a cross section taken perpendicular to the mounting direction of the developing container, for example, in FIG. 62. Also, the vertical direction is indicated by arrows in FIG. 62 and FIG. 63, and for example, a paper supply tray 6092 is disposed at a lower part of the printer 6010 and a fixing unit 6090 is disposed at an upper part of the printer 6010.

<Mounting and Dismounting Configuration>

Developing containers 6051, 6052, 6053, and 6054, which are configured as cartridges and are examples of developing devices, and a photoconductor unit 6075, which is an example of an image bearing member unit, can be mounted and dismounted with respect to the printer main unit 6010a, which is an example of an image forming apparatus main unit. The printer 6010 is configured by mounting the developing containers 6051, 6052, 6053, and 6054, and the photoconductor unit 75 to the printer main unit 6010a.

The printer main unit 6010a has a first opening cover 6010b that can be opened and closed, a second opening cover 6010c that can be opened and closed and that is provided further inward than the first opening cover 6010b, a photoconductor unit mounting and dismounting opening 10d through which the photoconductor unit 6075 can be mounted and dismounted, and a developing container mounting and dismounting opening 6010e serving as an opening through which the developing containers 6051, 6052, 6053, and 6054 can be mounted and dismounted.

Here, by opening the first opening cover 6010b, the user can mount and dismount the photoconductor unit 6075, which is devised as a cartridge, with respect to the printer main unit 6010a through the photoconductor unit mounting and dismounting opening 6010d. Further, by opening the second opening cover 6010c, the user can mount/dismount the developing containers 6051, 6052, 6053, and 6054, which are devised as cartridges, with respect to the printer main unit 6010a through the developing container mounting and dismounting opening 6010e.

<Configuration of the Printer 6010>

The configuration of the printer 6010 in a state in which the developing containers 6051, 6052, 6053 and 6054 and the photoconductor unit 75 are mounted to the printer main unit 6010a is described next.

As shown in FIG. 63, the printer 6010 according to the present embodiment includes a charging unit 6030, an exposing unit 6040, a developing container holding unit 6050, a first image transfer unit 6060, an intermediate image transfer member 6070, and a cleaning blade 6076. These units are arranged along the rotation direction of a photoconductor

6020, which is an example of an image bearing member bearing a latent image. The printer 6010 further includes a second image transfer unit 6080, a fixing unit 6090, a display unit 6095 constituted by a liquid-crystal panel and serving as a means for giving notifications to the user, a control unit 6100 for controlling these units and managing the operations of the printer, and a power source unit 6098 covered by a power source shielding member 6098a.

The photoconductor 6020, the charging unit 6030, the exposing unit 6040, the developing container holding unit 6050, the primary image transfer unit 6060, the intermediate image transfer member 6070, the cleaning blade 6076, the secondary image transfer unit 6080, the fixing unit 6090, the control unit 6100, and the power source unit 6098 are disposed at a certain spacing from the upstream side to the downstream side with respect to the mounting direction in a metal frame 6010f serving as a casing of the printer 6010. Moreover, between these elements and the frame 6010f, a metal stay 6010g is disposed on both ends in the direction intersecting with the mounting direction. Furthermore, the printer main unit 6010a is provided with mounting shielding members for shielding electromagnetic waves intruding from the outside, and the printer 6010 is covered substantially entirely by these shielding members. That is to say, the frame 6010f, which serves as the casing, and also the stay 6010g are mounting shielding members having the function of shielding members.

The photoconductor 6020 has a hollow cylindrical conductive base and a photoconductive layer formed on the outer circumferential surface of the conductive base, and is rotatable around its center axis. In the present embodiment, the photoconductor 6020 rotates clockwise, as indicated by the arrow in FIG. 63. The charging unit 6030 is a device for charging the photoconductor 6020. In the printer 6010 of the present embodiment, the photoconductor 6020, the cleaning blade 6076, and the charging unit 6030 are configured as one photoconductor unit 6075 provided with a waster toner container.

The exposing unit 6040 is a device for forming a latent image on the photoconductor 6020, which has been charged by irradiating a laser beam on the photoconductor 6020. The exposing unit 6040 includes, for example, a semiconductor laser, a polygon mirror, and an F-θ lens, and irradiates a modulated laser beam onto the charged photoconductor 6020 in accordance with image signals that have been input from a host computer not shown in the drawings, such as a personal computer or a word processor.

The developing container holding unit 6050 is a device for developing the latent image formed on the photoconductor 6020 using toner T, which is an example of a developer contained in the developing containers 6051, 6052, 6053, and 6054, that is, black (K) toner contained in a black developing container 6051, magenta (M) toner contained in a magenta developing container 6052, cyan (C) toner contained in a cyan developing container 6053, and yellow (Y) toner contained in a yellow developing container 6054.

This developing container holding unit 50 includes a rotation shaft 6050e and four mounting and dismounting sections 6050a, 6050b, 6050c and 6050d with respect to which the developing containers 6051, 6052, 6053 and 6054 can be mounted and dismounted and which are disposed at intervals of 90° in circumferential direction around the rotation shaft. The mounting and dismounting sections 6050a, 6050b, 6050c, and 6050d are moved by rotating the developing container holding unit 6050 around the rotation shaft 6050e. Each of the mounting and dismounting sections 6050a, 6050b, 6050c, and 6050d is provided with the same space, parti-

tioned by two neighboring wall sections **6050**/ of the four wall sections **6050**/ formed at intervals of 90° in four radial directions from the rotation shaft **6050e** provided in the middle of the developing container holding unit **6050**. That is to say, the mounting and dismounting section **6050a** with respect to which the black developing container **6051** can be mounted and dismounted, the mounting and dismounting section **6050b** with respect to which the magenta developing container **6052** can be mounted and dismounted, the mounting and dismounting section **6050c** with respect to which the cyan developing container **6053** can be mounted and dismounted, and the mounting and dismounting section **6050d** with respect to which the yellow developing container **6054** can be mounted and dismounted are disposed at intervals of 90° in circumferential direction around the rotation shaft **6050e** in the developing container holding unit **6050**.

It is possible to move the positions of the four developing containers **6051**, **6052**, **6053**, and **6054** that are held by moving the mounting and dismounting sections **6050a**, **6050b**, **6050c**, and **6050d** through the rotation of the developing container holding unit **6050** around the rotation shaft **6050e**. That is to say, the four developing containers **6051**, **6052**, **6053**, and **6054** can be rotated around the rotation shaft **6050e** while maintaining their relative positions. Then, when the developing containers **6051**, **6052**, **6053**, and **6054** are mounted to the mounting and dismounting sections **6050a**, **6050b**, **6050c**, and **6050d** and are moved to the developing position through the movement of the mounting and dismounting sections **6050a**, **6050b**, **6050c**, and **6050d**, the latent image carried by the photoconductor **6020** is developed with the toner contained in the respective developing containers **6051**, **6052**, **6053**, and **6054**. It should be noted that details of the developing containers are discussed later.

As shown in FIG. 65, the mounting and dismounting sections **6050a**, **6050b**, **6050c**, and **6050d** are each provided with coupling holes **6059** into which coupling protrusions provided on a coupling member **6590** (see FIG. 68) of the developing containers can be fitted, guiding sections **6056** for guiding the developing container into the mounting position by engaging with a guided section **6549** provided on the developing container that is inserted from the developing container mounting and dismounting opening **6010e**, and springs **6576** for urging the developing containers toward the outer circumferential direction of the developing container holding unit **6050**. For example, coupling pins **6595a** and **6595b** (see FIG. 72), which are examples of coupling protrusions provided on the coupling member **6590** of the yellow developing container **6054**, as shown in FIG. 66, are fitted into the coupling holes **6059** with which the mounting and dismounting section **6050d** is provided.

And as shown in FIG. 67, the guiding sections **6056** are provided on each of two wall sections **6050f** constituting the mounting and dismounting section. The guiding sections **6056** have perpendicular surfaces formed on the respective wall sections **6050f** and are arranged extending along the longitudinal direction of the yellow developing container **6054**, protruding on the side of the same space partitioned by two adjacent wall sections **6050f**. That is to say, the guiding sections **6056**, which are provided on adjacent wall sections **6050f** facing toward the same space, are formed such that their surfaces both face toward the rotation shaft **6050e** and their surfaces define an angle of substantially 90°. The yellow developing container **6054** is mounted by arranging the guided sections **6549** of the yellow developing container **6054** such that they are on the side of the rotation shaft **6050e**

with respect to the two perpendicular surfaces of the guiding sections **6056**, and inserting the guided sections **6549** along the guiding sections **6056**.

Moreover, as shown in FIG. 66 and FIG. 67, the mounting and dismounting sections **6050a**, **6050b**, **6050c**, and **6050d** are provided with springs **6576**. For example, the springs **6576** provided on the mounting and dismounting section **6050d** urge the yellow developing container **6054** toward the outer circumferential direction of the developing container holding unit **6050**. Thus, when the yellow developing container **6054** is inserted from the developing container mounting and dismounting opening **6010e** with the guided sections **6549** being arranged on the side of the rotation shaft **6050e** with respect to the perpendicular surfaces of the guiding sections **6056**, the yellow developing container **6054** is urged by the springs **6576** toward the outer circumferential direction. Moreover, as shown in FIG. 65, the mounting and dismounting sections **6050a**, **6050b**, **6050c**, and **6050d** are each provided with a positioning hole **6058** into which a positioning pin **6588** (see FIG. 68) of the respective developing container can be fitted. That is to say, by fitting the positioning pin **6588** provided on the yellow developing container **6054** into the positioning hole **6058** provided in the mounting and dismounting section **6050d**, the yellow developing container **6054** is mounted by positioning it in a predetermined position.

The primary image transfer unit **6060** is a device for transferring a single color toner image formed on the photoconductor **6020** to the intermediate image transfer member **6070**. When the four toner colors are successively transferred over one another, a full color toner image is formed on the intermediate image transfer member **6070**. This intermediate image transfer member **6070** is an endless belt that is rotatively driven at substantially the same circumferential velocity as the photoconductor **6020**.

The secondary image transfer unit **6080** is a device for transferring a single color toner image or a full color toner image formed on the intermediate image transfer member **6070** to a recording medium such as paper, film, or cloth. The fixing unit **6090** is a device for fusing the single color toner image or the full color toner image that has been transferred to the recording medium on the recording medium, such as paper, making it a permanent image.

The cleaning blade **6076** is made of rubber and is in contact with the surface of the photoconductor **6020**. The cleaning blade **6076** scrapes off and removes toner remaining on the photoconductor **6020**, after the toner image has been transferred to the intermediate image transfer body **6070** by the primary image transfer unit **6060**.

The photoconductor unit **6075** is provided between the primary image transfer unit **6060** and the exposing unit **6040**, and includes the photoconductor **6020**, the charging unit **6030**, the cleaning blade **6076**, and a waste toner container not shown in the drawings containing toner that has been scraped away by the cleaning blade **6076**.

The control unit **6100** is made of a main controller **6101** and a unit controller **6102**, as shown in FIG. 64. An image signal is input into the main controller **6101**, and in accordance with a command based on this image signal, the unit controller **6102** controls the various units, for example, to form the image.

<Operation of the Printer **6010**>

The operation of the printer **6010** configured as above is described below, referring to other structural components thereof as well.

129

First, when an image signal from a host computer not shown in the drawings is input into the main controller 6101 of the printer 6010 via an interface (I/F) 6112, the photoconductor 6020, developing rollers 6510 provided in the developing containers 6051, 6052, 6053, and 6054, and the intermediate image transfer member 6070 are rotated under the control of the unit controller 6102 based on a command from the main controller 6101. While rotating, the photoconductor 6020 is successively charged by the charging unit 6030 at a charging position.

The region of the photoconductor 6020 that has been charged is brought to an exposure position through rotation of the photoconductor 6020, and a latent image corresponding to image information of a first color, for example yellow Y, is formed at that region by the exposing unit 6040. Moreover, the developing container holding unit 6050 positions the yellow developing container 6054 containing the yellow (Y) toner at the developing position opposite the photoconductor 6020.

The latent image formed on the photoconductor 6020 is brought to a developing position through the rotation of the photoconductor 6020, and is developed with yellow toner by the yellow developing container 6054. Thus, a yellow toner image is formed on the photoconductor 6020.

The yellow toner image that is formed on the photoconductor 6020 is brought to the primary image transfer position through rotation of the photoconductor 6020 and is transferred to the intermediate image transfer member 6070 by the primary image transfer unit 6060. At this time, a primary image transfer voltage of a polarity that is opposite the toner charge polarity is applied to the primary image transfer unit 6060. It should be noted that throughout this operation, the secondary image transfer unit 6080 is removed from the intermediate image transfer member 6070.

The above process is repeated for a second color, a third color, and a fourth color, thereby transferring toner images of four colors corresponding to various image signals layered over one another onto the intermediate image transfer unit 6070. Thus, a full color toner image is formed on the intermediate image transfer member 6070.

The full color toner image that is formed on the intermediate image transfer member 6070 is brought to the secondary image transfer position through the rotation of the intermediate image transfer member 6070 and is transferred to a recording medium by the secondary image transfer unit 6080. It should be noted that the recording medium is carried from the paper supply tray 6092 to the secondary image transfer unit 6080 via a paper supply roller 6094 and registration rollers 6096. Also, when performing the image transfer operation, the secondary image transfer unit 6080 is pressed against the intermediate image transfer member 6070 while applying a secondary image transfer voltage to it.

The fixing unit 6090 heats and applies pressure to the full color toner image that has been transferred to the recording medium, thus fusing it to the recording medium. On the other hand, after the photoconductor 6020 has passed the primary image transfer position, the toner adhering to its surface is scraped off by the cleaning blade 6076 and it is provided with a charge for forming the next latent image. The toner that is scraped off is collected in the waste toner container.

==Overview of the Control Unit==

The configuration of the control unit 6100 is described next, with reference to FIG. 64. The control unit 6100 includes the main controller 6101 and the unit controller 6102.

130

The main controller 6101 includes a CPU 6111, an interface 6112 for connection to a computer not shown in the drawings, an image memory 6113 for storing image signals input from the computer, a main controller-side memory 6114 made of an EEPROM 6114a that can be rewritten electrically, a RAM 6114b, and a program ROM or the like in which a program for the various kinds of control is stored.

The CPU 6111 of the main controller 6101 controls the reading in and the reading out of image data that has been input via the interface into the image memory 6113, and performs the control of the overall apparatus in synchronization with the CPU 6120 of the unit controller 6102 based on the control signals input from the computer.

The unit controller 6102 includes the CPU 6120, a unit controller-side memory 6116 including an EEPROM 6116a that can be rewritten electrically, a RAM and a program ROM or the like in which a program for the various kinds of control is stored, as well as drive control circuits or the like for performing drive control of the various units of the entire device (the charging unit 6030, the exposing unit 6040, the developing container holding unit 6050, the primary image transfer unit 6060, the photoconductor unit 6075, the secondary image transfer unit 6080, the fixing unit 6090, and the display unit 6095).

The CPU 6120 of the unit controller 6102 is electrically connected to the various drive control circuits and controls the various drive control circuits in accordance with control signals from the CPU 6111 of the main controller 6101. That is to say, while the state of the units is detected by receiving signals from sensors or the like provided in each of the units, the units are controlled in accordance with signals input from the main controller 6101.

Also, the CPU 6120 provided in the unit controller 6102 is connected to a non-volatile storage element (hereinafter, also referred to as "main unit-side memory") 6122 such as a serial EEPROM via the serial interface (I/F) 6121. This main unit-side memory 6122 stores data that is necessary for the control of the apparatus.

Furthermore, the CPU 6120 is capable of wirelessly communicating with communication units 6051a, 6052a, 6053a, and 6054a, which serve as element units and are respectively provided in the developing containers 6051, 6052, 6053, and 6054, via the serial interface 6121, a communication control module 6123, and an antenna unit 6124 serving as an apparatus-side antenna. Through the communication of the antenna unit 124 and the communication units 6051a, 6052a, 6053a, and 6054a, the control unit 6100 can write information into the communication units 6051a, 6052a, 6053a, and 6054a provided in the developing containers 6051, 6052, 6053, and 6054 as well as read in information from the communication units 6051a, 6052a, 6053a, and 6054a provided in the developing containers 6051, 6052, 6053, and 6054. The communication units 6051a, 6052a, 6053a, and 6054a are explained further below.

==Overview of the Developing Containers==

The configuration and operation of the developing containers 6051, 6052, 6053, and 6054 is explained next, using FIG. 68 to FIG. 72. FIG. 68 is a perspective view of the yellow developing container 6054. FIG. 69 is a cross-sectional view showing the main structural components of the yellow developing container 6054. FIG. 70 is a perspective view of a developing roller 6510 provided with rolls 6574. FIG. 71 is a front view of the coupling member 6590. FIG. 72 is a perspective view showing the rear side of the coupling member 6590. It should be noted that the cross-sectional view in FIG. 69 shows a cross section of the yellow developing container

131

6054 taken along a plane that is perpendicular to the longitudinal direction shown in FIG. 68. Moreover, in FIG. 69, like in FIG. 62, the vertical direction is indicated by arrows, and for example, the center axis of the developing roller **6510** is lower than the center axis of the photoconductor **6020**. Also, in FIG. 69, the yellow developing container **6054** is shown positioned at a developing position that is in opposition to the photoconductor **6020**.

The black developing container **6051** containing black (K) toner, the magenta developing container **6052** containing magenta (M) toner, the cyan developing container **6053** containing cyan (C) toner, and the yellow developing container **6054** containing yellow (Y) toner can be mounted to the developing container holding unit **6050**, but since the configuration and the operation of each of the developing containers is the same, explanations are given only for the yellow developing container **6054** in the following.

<Internal Configuration of the Yellow Developing Container **6054**>

First, the configuration of the yellow developing container **6054** is described. The yellow developing container **6054** includes the developing roller **6510**, which is an example of a developer-carrying member, a toner containing section **6530**, a housing **6540** containing toner T, a toner supply roller **6550**, a regulating blade **6560**, a sealing member **6520**, a positioning shaft (also referred to as "positioning pin" in this embodiment) **6588**, which is an example of a positioning member (positioning section), and a coupling member **6590**.

The developing roller **6510** bears toner T and carries it to the developing position opposite the photoconductor **6020**, and develops the latent image carried by the photoconductor **6020** with the toner T carried to the developing position. This developing roller **6510**, which is made of metal, is fabricated from an aluminum alloy, such as 5056 aluminum alloy or 6063 aluminum alloy, or an iron alloy such as STKM, and may be nickel-plated or chromium-plated if necessary. As shown in FIG. 70, the developing roller **6510** includes a large-diameter section **6510a** and axle sections **6510b**.

Moreover, as shown in FIG. 68, the developing roller **6510** is supported by the housing **6540** at its two ends in longitudinal direction, that is, at the axle sections **6510b**, and can be rotated around its center axis. As shown in FIG. 69, the developing roller **6510** rotates in a direction (the counter-clockwise direction in FIG. 69) that is opposite to the rotation direction of the photoconductor **6020** (the clockwise direction in FIG. 69). Its center axis is lower than the center axis of the photoconductor **6020**.

Also, as shown in FIG. 69, in a state where the yellow developing container **6054** is in opposition to the photoconductor **6020**, there is a gap between the developing roller **6510** and the photoconductor **6020**. That is to say, the yellow developing container **6054** develops the latent image formed on the photoconductor **6020** in a noncontacting manner. It should be noted that during the development of the latent image formed on the photoconductor **6020**, an alternating electric field is formed between the developing roller **6510** and the photoconductor **6020**.

Furthermore, as shown in FIG. 70, rolls **6574**, which are an example of distance holding members, are formed on both ends in longitudinal direction of the developing roller **6510**. When the developing containers **6051**, **6052**, **6053** and **6054** are positioned in the developing position, these rolls **6574** have the function of coming into contact with the photoconductor **6020** and thereby holding a constant distance between the photoconductor **6020** and the developing roller **6510**. The rolls **6574** are slid rotatably onto the axle sections **6510b**. The

132

outer diameter of the rolls **6574** is larger than the outer diameter of the large-diameter section **6510a**. Therefore, it is possible to hold a constant distance between the developing roller **6510** and the photoconductor **6020** by rotating the rolls **6574** while they contact the photoconductor **6020**.

The sealing member **6520** prevents the toner T in the yellow developing container **6054** from leaking to the outside, and also collects toner T on the developing roller **6510**, after it has passed the developing position, into the developing device without scraping it off. This sealing member **6520** is a seal made of polyethylene film or the like. The sealing member **6520** is supported by a seal support metal plate **6522**, and is attached to the housing **6540** via the seal support metal plate **6522**. Furthermore, a seal biasing member **6520** made of Moltopren or the like is provided on the side of the sealing member **6524** that is opposite to its developing roller **6510** side, and due to the elasticity of the seal biasing member **6524**, the sealing member **6520** is pressed against the developing roller **6510**. It should be noted that the contact position where the sealing member **6520** contacts the developing roller **6510** is above the center axis of the developing roller **6510**.

The housing **6540** is fabricated by welding together a plurality of integrally molded housing sections, namely an upper housing section **6542** and a lower housing section **6544**. A partitioning wall **6545** for partitioning the inside of the housing, which protrudes from the inner wall to the inside (vertically in FIG. 69), partitions the inside of the housing **6540** into two toner containing sections **6530**, namely a first toner containing section **6530a** and a second toner containing section **6530b**. It should be noted that the housing **6540** has a housing opening **6572** at its bottom, and the developing roller **6510** is arranged such that a portion of it is exposed in this housing opening **6572**. Moreover, a communication unit **6054a** is attached to the housing **6540**. The configuration of this communication unit **6054a** and the position at which it is attached to the housing **6540** are explained later.

A second side wall **6547**, which is arranged on the forward side of the printer main unit **6010a** in the longitudinal direction of the housing **6540**, is provided with attachment protrusions **6581a** and **6581b** (see FIG. 71). The attachment protrusion **6581a** can be fitted into an attachment hole **6593a** of the later-explained coupling member **6590**, and the attachment protrusion **6581b** can be fitted into an attachment hole **6593b** of the coupling member **6590**. The attachment protrusions **6581a** and **6581b** have a circular cross section.

Moreover, the toner containing section **6530** may be provided with a stirring member for stirring the toner T, but in the present embodiment, the developing containers (the black developing container **6051**, the magenta developing container **6052**, the cyan developing container **6053** and the yellow developing container **6054**) rotate with the rotation of the developing container holding unit **6050**, and this stirs the toner T inside the developing containers, so that the toner containing section **6530** is not provided with a stirring member.

The toner supply roller **6550** is provided in the above-mentioned first toner containing section **6530a** and not only supplies toner T that is contained in this first toner containing section **6530a** to the developing roller **6510**, but also scrapes off, from the developing roller **6510**, toner T that has remained on the developing roller **6510** after developing. The toner supply roller **6550** is made of polyurethane foam, for example, and is in contact with the developing roller **6510** in a state of elastic deformation. The toner supply roller **6550** is disposed at the bottom of the toner containing section **6530**, and the toner T contained in the toner containing section **6530**

is supplied to the developing roller 6510 by this toner supply roller 6550 at the bottom of the toner containing section 6530. The toner supply roller 6550 rotates in a direction (the clockwise direction in FIG. 69) that is opposite the rotation direction of the developing roller 6510 (the counterclockwise direction in FIG. 69). Its center axis is lower than the rotation center axis of the developing roller 6510.

The regulating blade 6560 applies a charge to the toner T borne on the developing roller 6510 and regulates the layer thickness of the toner T borne on the developing roller 6510. The regulating blade 6560 includes a rubber part 6560a and a rubber supporting part 6560b. The rubber part 6560a is made of silicone rubber or urethane rubber, for example, and the rubber supporting part 6560b is a thin plate of phosphor bronze or stainless steel, for example, and has elasticity. The rubber part 6560a is supported by the rubber supporting part 6560b, and the rubber supporting part 6560b is attached to the housing 6540 via a blade support metal plate 6562, with one end of the rubber supporting part 6560b being supported by the blade support metal plate 6562. Also, a blade backing member 6570 made of Moltopren or the like is provided on the side of the regulating blade 6560 that is opposite the side of the developing roller 6510.

Here, the rubber part 6560a is pressed against the developing roller 6510 by the elastic force due to the bending of the rubber supporting part 6560b. The blade backing member 6570 prevents the toner T from entering in between the rubber supporting part 6560b and the housing 6540, and stabilizes the elasticity due to the bending of the rubber supporting part 6560b while pressing the rubber part 6560a against the developing roller 6510 by urging the rubber part 6560a toward the developing roller 6510 from directly behind the rubber part 6560a. Consequently, the blade backing member 6570 makes the contact of the rubber part 6560a with the developing roller 6510 more uniform.

The end of the regulating blade 6560 on the side opposite the side supported by the blade support metal plate 6562, that is, its front end, is not in contact with the developing roller 6510, and a portion thereof removed from this front end by a predetermined distance is in contact with the developing roller 6510 over a certain width. That is to say, the regulating blade 6560 does not contact against the developing roller 6510 at its edge but rather at a mid section thereof. Also, the regulating blade 6560 is disposed such that its front end is facing upstream with respect to the direction in which the developing roller 6510 rotates, and is in so-called counter contact. It should be noted that the contact position where the regulating blade 6560 contacts the developing roller 6510 is below the center axis of the developing roller 6510 and is below the center axis of the toner supply roller 6550.

<Configuration of the Positioning Member (Section)>

The following is a description of the configuration of the positioning pin 6588. As shown in FIG. 68, the positioning pin 6588 is provided on one end in longitudinal direction of the yellow developing container main unit, which is an example of a developing device main unit, that is, on the downstream side with respect to the direction in which the developing container is mounted.

This positioning pin 6588 has the function of positioning the yellow developing container main unit with respect to the mounting and dismounting section 6050d by engaging the mounting and dismounting section 6050d, or more specifically by fitting into the positioning hole 6058 provided on the mounting and dismounting section 6050d, as shown in FIG. 66, when the yellow developing container 6054 is mounted to the mounting and dismounting section 6050d.

Moreover, the positioning pin 6588, which is made of metal, is arranged such that its axial direction extends in the longitudinal direction of the developing container main unit. One end of the positioning pin 6588 is fixed to a first side wall 5 6546 of the housing 6540, on the downstream side with respect to the mounting direction. The front end of the positioning pin 6588 is tapered, so that it can be easily fitted into the positioning hole 6058 of the mounting and dismounting section 6050d.

10 <Configuration of the Coupling Member>

The configuration of the coupling member 6590 is described next. As shown in FIG. 68, the coupling member 6590 is attached to the upstream side, with respect to the mounting direction, of the yellow developing container main unit.

As shown in FIG. 72, the coupling member 6590 is provided with coupling pins 6595a and 6595b, which are an example of coupling protrusions that can be fitted into the coupling holes 6059 of the mounting and dismounting section 20 6050d. When the yellow developing container 6054 is mounted to the mounting and dismounting section 6050d, the coupling pins 6595a and 6595b are fitted into the coupling holes 6059 provided in the mounting and dismounting section 6050d. Thus, when the yellow developing container 6054 is mounted to the mounting and dismounting section 6050d, the coupling member 6590 is coupled to the mounting and dismounting section 6050d. It should be noted that when the coupling member 6590 is coupled to the mounting and dismounting section 6050d, the movement of the coupling member 6590 with respect to the mounting and dismounting section 30 6050d is restricted.

Furthermore, as shown in FIG. 71, the coupling member 35 6590 includes an attachment hole 6593a into which the attachment protrusion 6581a provided on the second side wall 6547 on the other end in longitudinal direction of the housing 6540, that is, the upstream side with respect to the mounting direction of the developing container, can be fitted, and an attachment hole 6593b into which the attachment protrusion 40 6581b can be fitted. When the attachment protrusion 6581a is fitted into the attachment hole 6593a and the attachment protrusion 6581b is fitted into the attachment hole 6593b, the coupling member 6590 is attached to the side wall on the upstream side in the mounting direction of the housing 6540, that is, of the developing container, by screwing on 45 screws 6598 via the coupling member 6590 with respect to screw holes provided in the attachment protrusion 6581a and the attachment protrusion 6581b, as shown in FIG. 66.

Moreover, as shown in FIG. 71, the attachment hole 50 6593a and the attachment hole 6593b have a substantially elliptical cross section. The attachment hole 6593a and the attachment hole 6593b are provided such that the directions of the major axes of the substantially elliptical cross sections are the same direction. Moreover, as noted above, the cross section of the attachment protrusion 6581a is circular. Consequently, the attachment hole 6593a allows movement of the attachment protrusion 6581a, which is fitted into the attachment hole 6593a, within the attachment hole 6593a. Similarly, the attachment hole 6593b allows movement of the attachment protrusion 6581b, which is fitted into the attachment hole 6593b, within the attachment hole 6593b.

That is to say, the attachment hole 6593a allows movement of the attachment protrusion 6581a within the attachment hole 6593a in the direction of the major axis of its substantially elliptical cross section, and the attachment hole 6593b allows movement of the attachment protrusion 6581b within the attachment hole 6593b in the direction of the major axis of

135

its elliptical cross section. It should be noted that the movement of the attachment protrusion **6581a** within the attachment hole **6593a** and the movement of the attachment protrusion **6581b** within the attachment hole **6593b** occur at the same timing. Thus, the coupling member **6590** is attached in such a manner that its relative position to the developing container main unit can be changed.

<Operation of the Yellow Developing Container **6054**>

Next, the operation of the yellow developing container **6054** is described. In the yellow developing container **6054** configured in this manner, the toner T that is contained in the toner containing section **6530** is supplied to the developing roller **6510** by rotating the toner supply roller **6550**.

As the developing roller **6510** rotates, the toner T that is supplied to the developing roller **6510** is brought to the contact position of the regulating blade **6560**, and when it passes that contact position, the layer thickness of the toner T is regulated, and a charge is applied to it. The toner T on the developing roller **6510**, whose layer thickness has been regulated and which has been charged, is brought to the developing position in opposition to the photoconductor **6020** by further rotation of the developing roller **6510**, and is supplied for the development of the latent image formed on the photoconductor **6020** in an alternating electric field at the developing position.

The toner T on the developing roller **6510** that has passed the developing position due to further rotation of the developing roller **6510** passes the upper sealing member **6520** and is collected in the developing device without being scraped off by the upper sealing member **6520**. Moreover, the toner T that still remains on the developing roller **6510** is stripped off by the toner supply roller **6550**.

====The Developing Position, Communication Position and Mounting and Dismounting Position of the Developing Containers====

As mentioned above, the developing containers **6051**, **6052**, **6053**, and **6054** are moved together with the movement of the mounting and dismounting sections **6050a**, **6050b**, **6050c**, and **6050d**. At that time, the mounting and dismounting sections are moved such that the developing containers are positioned in predetermined positions. Such predetermined positions are the developing position, serving as a first position, the communication position, serving as a second position, and the mounting and dismounting position. Since the developing position, the communication position and the mounting and dismounting position of each of the developing containers are the same, the developing position, the communication position and the mounting and dismounting position of the yellow developing container **6054** are explained in the following with reference to FIGS. 73A to 73D. FIG. 73A is a diagram showing the developing container holding unit **6050** in a state where the yellow developing container **6054** is positioned at the developing position. FIG. 73B is a diagram showing the developing container holding unit **6050** in a state where the yellow developing container **6054** is positioned at the communication position. FIG. 73C is a diagram showing the developing container holding unit **6050** in a state where the yellow developing container **6054** is positioned at the mounting and dismounting position. FIG. 73D is a diagram showing a state where the developing container holding unit **6050** is positioned in its home position.

In the state shown in FIG. 73A, the yellow developing container **6054** is positioned at the developing position in which the developing roller **6510** is in opposition to the photoconductor **6020**. In this state, the developing roller **6510** is able to develop the latent image borne on the photoconductor

136

6020. In the state in which the yellow developing container **6054** is positioned in the developing position, as noted above, the springs **6576** provided in the mounting and dismounting section **6050d** bias the yellow developing container main unit **6054** towards the outer circumferential side. Due to this biasing force of the springs **6576**, the rolls **6574** contact against the photoconductor **6020**. It should be noted that when the photoconductor **6020** is installed in a slanted manner with respect to the printer main unit **6010a**, then the yellow developing container main unit moves with respect to the coupling member **6590** when the yellow developing container **6054** is positioned in the developing position, that is, the attachment protrusion **6581a** of the yellow developing container main unit moves in the major axis direction within the attachment hole **6593a** of the coupling member and the attachment protrusion **6581b** of the yellow developing container main unit moves in the major axis direction within the attachment hole **6593b** of the coupling member **6590**, so that the rolls **6574** with which the yellow developing container main unit is provided contact suitably against the photoconductor **6020**. During this, the relative position of the developing container main unit and the coupling member **6590** is changed in accordance with the biasing force of the springs **6576**. It should be noted that in a state in which the yellow developing container **6054** is positioned in the developing position, the magenta developing container **6052** is positioned in the communication position.

Furthermore, when the developing container holding unit **6050** is rotated for a predetermined angle in Z-direction in FIG. 73A from the state shown in FIG. 73A around its rotation shaft **6050e**, then the state shown in FIG. 73B is achieved. In the state shown in FIG. 73B, the yellow developing container **6054** is positioned in the communication position. In this state, the communication unit **6054a** provided on the yellow developing container **6054** opposes the antenna unit **6124** in a noncontacting manner. This communication unit **6054a** can then communicate with the antenna unit **6124**. Furthermore, when the yellow developing container **6054** is positioned in the communication position, the rolls **6574** of the yellow developing container **6054** do not contact against members on the side of the printer main unit **6010a**. It should be noted that when the yellow developing container **6054** is positioned in the communication position, the black developing container **6051** is positioned in the developing position. Therefore, the communication between the antenna unit **6124** and the communication unit can take place while the black developing container **6051** develops the latent image borne on the photoconductor **6020**.

Furthermore, when the developing container holding unit **6050** is rotated around its rotation shaft **6050e** for a predetermined angle in Z-direction in FIG. 73B from the state shown in FIG. 73B, then the state shown in FIG. 73C is achieved. In the state shown in FIG. 73C, the yellow developing container **6054** is positioned in the mounting and dismounting position. In this state, the yellow developing container **6054** can be mounted and dismounted via the developing container mounting and dismounting opening **6010e**, that is, the yellow developing container **6054** can be mounted to the mounting and dismounting section **6050d** or it can be dismounted from the mounting and dismounting section **6050d**.

It should be noted that after the power source of the printer main unit **6010a** has been turned on and an initialization operation has been performed, and before the printer **6010** forms an image, the developing container holding unit **6050** is positioned in the home position shown in FIG. 73D.

====Configuration of the Communication Unit====

The configuration of the communication unit with which in the developing container is provided as well as the configuration for sending and receiving data is described next with reference to FIG. 74, FIG. 75, and FIG. 76. FIG. 74 is a plan view showing the configuration of the communication unit. FIG. 75 is a block diagram illustrating the internal configuration of the communication unit and the send/receive section. FIG. 76 is a diagram illustrating the information stored in a memory cell 6054h of the communication unit 6054a.

Communication units are attached respectively to the developing containers 6051, 6052, 6053, and 6054, but since the configuration of the communication units attached to the developing containers and the positions at which the communication units are attached to the developing container main units are the same for all developing containers, the following is an explanation taking the communication unit 6054a attached to the yellow developing container 6054 as an example.

When the yellow developing container 6054 is mounted to the mounting and dismounting section 6050d, the communication unit 6054a can communicate with the antenna unit 6124 on the side of the printer main unit 6010a in a noncontacting manner. As mentioned above, the yellow developing container 6054 is moved by the movement of the mounting and dismounting section 6050d. When the yellow developing container 6054 has been moved to the communication position, which is different from the developing position, the communication unit 6054a communicates in a noncontacting manner with the antenna unit 6124 with which the printer main unit 6010a is provided. The communication unit 6054a is provided inward of the antenna unit 6124 in radial direction with respect to the center of the rotation shaft 6050e of the developing container holding unit 6050.

The communication unit 6054a includes a thin plate-shaped substrate 6054i serving as a substrate made of a thin plate-shaped piece of plastic that is flexible in its longitudinal direction, an antenna 6054d serving as a first antenna made by arranging copper foil in a rectangular planar coil shape, antenna terminals 6054j provided on both ends of the antenna, a non-contact IC chip 6054b including a memory and serving as an element for communicating with an external antenna, two coupling sections 6054k made of aluminum that connect the chip terminals of the non-contact IC chip 6054b with the antenna terminals 6054j, and a film-shaped protective sheet 6054m covering these elements, sandwiching them together with the thin plate-shaped substrate 6054i.

As shown in FIG. 74, one antenna terminal 6054j of the antenna 6054d is arranged at one end in the longitudinal direction of the rectangular thin plate-shaped substrate 6054i, the antenna 6054d is wrapped about ten times in a coil shape along the outer shape of the thin plate-shaped substrate 6054i, and the other antenna terminal 6054j is provided to the inner side of the antenna 6054d. The outer antenna terminal 6054j and the inner antenna terminal 6054j are both provided on the same side in the longitudinal direction of the thin plate-shaped substrate 6054i. On the thin plate-shaped substrate 6054i, the ten copper foil structures of the antenna 6054d are lined up next to each other along the vertical and horizontal edges of the rectangular shape, and are divided into five each at one corner on that side of the thin plate-shaped substrate 6054i where the antenna terminals 6054j are provided, the non-contact IC chip 6054b being arranged between these. Furthermore, two coupling sections 6054k connecting chip terminals (not shown in the drawings) provided on the non-contact IC chip 6054b with the antenna terminals 6054j are provided, respectively straddling five copper foil structures.

That is to say, on the thin plate-shaped substrate 6054i, the non-contact IC chip 6054b, two antenna terminals 6054j, and two coupling sections 6054k are provided on one end in longitudinal direction, and the copper foil structures serving as the antenna 6054d are guided around the remaining region, except for the center.

As shown in FIG. 68, the communication unit 6054a is provided between the positioning pin 6588 and the coupling member 6590 in the longitudinal direction of the yellow developing container main unit on the side of the positioning pin 6588, that is, on the downstream side with respect to the direction in which the yellow developing container 6054 is mounted. In this situation, the communication unit 6054a is arranged such that the end where the non-contact IC chip 6054b is provided is arranged on the upstream side of the communication unit 6054a with respect to the mounting direction.

Moreover, the communication unit 6054a is attached to an outer surface 6543 of the housing 6540, that outer surface 6543 extending in the longitudinal direction of the housing 6540. Here, the outer surface 6543 refers to the part of the housing 6540 corresponding to the dash-dotted line in FIG. 69. It should be noted that this outer surface 6543 includes a circularly arc-shaped surface 6543a, whose cross section through a perpendicular plane that is perpendicular to the longitudinal direction of the housing 6540 is circularly arc-shaped. This circularly arc-shaped surface 6543a is arranged such that its circular arc extends along the rotation direction of the developing container holding unit 6050 when the yellow developing container 6054 is mounted to the mounting and dismounting section 6050d. As shown in FIG. 69, the communication unit 6054a is attached at a position of the circularly arc-shaped surface 6543a that is furthest removed from the developing roller 6510.

FIG. 77 is a diagram illustrating the antenna unit 6124. FIG. 78 is a diagram illustrating how the antenna unit is installed in a holder. The antenna unit 6124 provided on the side of the printer main unit 6010a includes a substrate 6124a that is formed on a plate material made of resin, an antenna 6124b serving as a second antenna that is made of copper foil wrapped in a planar coil shape along the outer shape of the substrate 6124a, substantially as in the communication unit 6054a, antenna terminals 6124c provided at the ends of the antenna 6124b, and a film-shaped protective sheet 6124d made of resin. Furthermore, the two antenna terminals 6124c are each connected to a wire 6124e and connected to the control unit 6100 via the communication control module 6123. Here, the antenna unit 6124 of the present embodiment is configured having a protective sheet 6124d, but it is not necessarily required to provide the protective sheet 6124d.

When the mounted yellow developing container 6054 has been arranged in the communication position, the antenna 6054d of the communication unit 6054a and the antenna 6124b of the antenna unit 6124 are arranged at positions facing each other. Moreover, the antenna unit 6124 is fixed via a holder 6125 made of resin to the printer main unit 6010a.

The holder 6125 is box-shaped, covering the surroundings of the antenna unit 6124 as well as the sides of the substrate 6124a and open on one side, and is arranged such that the antenna 6124b faces the outside from the open side. At the edges of the open sides of the holder 6125, flexible tongues 6125b protruding toward the inside are provided on opposing side walls 6125a. The antenna unit 6124 is accommodated inside the box-shaped holder 6125 and is held there by the tongues 6125b. That is to say, the antenna unit 6124 is held

only by the holder **6125** made of resin, so that metal components such as screws are not required to fasten the antenna unit **6124**.

If the communication unit **6054a** and the antenna unit **6124** are in a predetermined positional relationship, for example, if they are within a distance of 10 mm of one another, then information can be exchanged in a noncontacting manner between the two. The communication unit **6054a** is overall very compact and thin, and one of its sides is adhesive and can be adhered to an object as a seal. It is also called a memory tag, for example, and is commercially available in various forms.

As shown in FIG. 75, the non-contact IC chip **6054b** includes a resonance capacitor **6054c**, a rectifier **6054e**, a signal analysis section RF (Radio Frequency) **6054f**, a controller **6054g**, and the memory cell **6054h**. The memory cell **6054h** is a non-volatile memory that can be electrically read and written, such as a NAND flash-ROM, and is capable of storing information that has been written on it and reading stored information from the outside. The antenna **6054d** of the communication unit **6054a** and the antenna unit **6124** communicate wirelessly with one another, so that information stored in the memory cell **6054h** can be read and information can be written to the memory cell **6054h**. Also, the high-frequency signals that are generated by the communication control module **6123** of the printer main unit **6010a** are induced as a high-frequency magnetic field via the antenna unit **6124**. This high-frequency magnetic field is absorbed via the antenna **6054d** of the communication unit **6054a** and is rectified by the rectifier **6054e**, thus serving as a DC power source for driving the circuits in the non-contact IC chip **6054b**.

The memory cell **6054h** of the communication unit **6054a** stores various types of information, as shown in FIG. 76. The address 00H stores unique ID information for each communication unit, such as the serial number of the communication unit, the address 01H stores the date when the yellow developing container **6054** was manufactured, the address 02H stores information for specifying the destination of the yellow developing container **6054**, the address 03H stores information for specifying the manufacturing line on which the yellow developing container **6054** was manufactured, the address 04H stores information for specifying models with which the yellow developing container **6054** is compatible, the address 05H stores remaining toner amount information as information indicating the amount of toner that is contained in the yellow developing container **6054**, and the address 06H and subsequent regions also store information as appropriate.

The ID information that is stored in the memory cell **6054h** of the communication unit **6054a** can be written at the time that the storage communication unit is manufactured in the factory. By reading this ID information with the printer main unit **6010a**, it is possible to identify the individual communication units **6054a**, **6051a**, **6052a**, and **6053a**.

It should be noted that it is also possible to let the antenna unit **6124** communicate wirelessly with the communication unit **6054a** not only when the developing container holding unit **6050** is standing still but also when the developing container holding unit **6050** is moving. That is, the antenna unit **6124** may be able to communicate wirelessly with the communication unit **6054a** even when the communication unit **6054a** is moving.

First Working Example

==Operation of Mounting the Developing Containers==

FIG. 79 is a diagrammatic view, taken from A2 in FIG. 62, showing the positional relationship between a developing container and the printer main unit when mounting the developing container to the printer main unit **6010a**. Also here, the explanations concern the mounting of the yellow developing container **6054**, but the mounting operation of the other developing containers is the same.

When the yellow developing container **6054** is mounted to the printer main unit **6010a**, the user operates the printer main unit **6010a**, whose power has been turned on, and enters a command for mounting the yellow developing container **6054**. Through this operation, the developing container holding unit **6050** is rotated such that the mounting and dismounting section **6050d**, to which the yellow developing container **6054** is supposed to be mounted, becomes positioned in the mounting and dismounting position. After the developing container holding unit **6050** has stopped, the user opens the first opening cover **6010b** and the second opening cover **6010c** of the printer main unit **6010a**.

Next, the yellow developing container **6054** is passed through the developing container mounting and dismounting opening **6010e** of the printer main unit **6010a** from the side of the positioning pin **6588**, with the side of the coupling member **6590** facing frontward.

Then, it is slowly inserted up to a position where the guided sections **6549** at the front end side of the yellow developing container **6054** engage the guiding sections **6056** on the side of the printer main unit **6010a**. Even though at this time a portion of the communication unit **6054a** has passed through the developing container mounting and dismounting opening **6010e**, the non-contact IC chip **6054b** has not yet reached the developing container mounting and dismounting opening **6010e**.

After this, the yellow developing container **6054** is moved downstream in the carry direction, while the guided sections **6549** are slid into the guiding sections **6056**, and the positioning pin **6588** is fitted into the positioning hole **6058**, whereas the coupling pins **6595a** and **6595b** are fitted into the coupling holes **6059**. Finally, after shutting the second opening cover **6010c** and then shutting the first opening cover **6010b**, the developing container holding unit **6050** is rotated and stopped at its home position.

That is to say, in the developing containers **6051**, **6052**, **6053** and **6054** of the this embodiment, the non-contact IC chips **6051b**, **6052b**, **6053b**, and **6054b** are arranged at one end of rectangular thin plate-shaped bases **6051i**, **6052i**, **6053i**, **6054i** of the communication units **6051a**, **6052a**, **6053a**, and **6054a**, and the end on the side were the non-contact IC chips **6051b**, **6052b**, **6053b**, and **6054b** are arranged is positioned on the upstream side with respect to the mounting direction of the developing containers **6051**, **6052**, **6053**, and **6054**. Therefore, a distance of the extent that the antennas **6051d**, **6052d**, **6053d** and **6054d** of the communication units **6051a**, **6052a**, **6053a**, and **6054a** are disposed on the downstream side with respect to the mounting direction is ensured between the non-contact IC chips **6051b**, **6052b**, **6053b**, and **6054b** and the front end of the developing container. That is to say, when the developing containers **6051**, **6052**, **6053**, and **6054** are mounted to the printer main unit **6010a**, the thin plate-shaped bases **6051i**, **6052i**, **6053i** and **6054i** of the communication units **6051a**, **6052a**, **6053a**, and **6054a** are positioned further downstream than at least the non-contact IC chips **6051b**, **6052b**, **6053b**, and **6054b**, and

the non-contact IC chips **6051b**, **6052b**, **6053b**, and **6054b** are not positioned at the front-most end of the developing containers **6051**, **6052**, **6053**, and **6054**. Therefore, there is little risk that the user inadvertently damages the non-contact IC chips **6051b**, **6052b**, **6053b**, or **6054b** by bumping them against the developing container mounting and dismounting opening **6010e**, when mounting the developing containers **6051**, **6052**, **6053**, and **6054** to the printer main unit **6010a**. Thus, the user can mount the developing containers **6051**, **6052**, **6053**, and **6054** without paying excessively close attention. Thus, it is possible to realize developing containers **6051**, **6052**, **6053**, and **6054** that are easy to mount.

More particularly, since the communication units **6051a**, **6052a**, **6053a**, and **6054a** communicate via the antenna unit **6124**, which is provided on the printer main unit **6010a**, the communication units **6051a**, **6052a**, **6053a**, and **6054a** and the antenna unit **6124** are arranged at positions where they come close to each other, so that there is little space around the communication units **6051a**, **6052a**, **6053a**, and **6054a** when the developing containers **6051**, **6052**, **6053**, and **6054** are mounted to the printer main unit **6010a**. However, when the developing containers **6051**, **6052**, **6053** and **6054** have been inserted, the positions where the non-contact IC chips **6051b**, **6052b**, **6053b**, and **6054b** are passed through have already been passed by the front end side of the developing containers **6051**, **6052**, **6053**, and **6054**, and the guided sections **6549** are guided by the guiding sections **6056**, so that the risk is small that the non-contact IC chips **6051b**, **6052b**, **6053b**, and **6054b** are damaged while inserting the developing containers **6051**, **6052**, **6053**, and **6054**.

Furthermore, since the risk that the non-contact IC chips **6051b**, **6052b**, **6053b**, and **6054b** are damaged while mounting the developing containers **6051**, **6052**, **6053**, and **6054**, it is possible to use a film-shaped protective sheet **6054m**, instead of providing a thick protection cover on the surface of the communication units **6051a**, **6052a**, **6053a**, and **6054a**. For this reason, the communication distance to the antenna unit **6124** facing the communication units during communication can be made shorter, so that it is possible to ensure favorable communication conditions.

Moreover, as shown in FIG. 68, in the developing containers **6051**, **6052**, **6053**, and **6054** of the above-described embodiment, the communication units **6051a**, **6052a**, **6053a**, and **6054a** are provided at the end in the longitudinal direction of the main units of the developing containers **6051**, **6052**, **6053**, and **6054**, that is, on the downstream side, with respect to the mounting direction, of the developing containers **6051**, **6052**, **6053**, and **6054**. And when the developing containers **6051**, **6052**, **6053**, and **6054** are mounted to the printer main unit **6010a**, also the positioning pins **6588**, which determine the relative position of the printer main unit **6010a** and the developing containers **6051**, **6052**, **6053**, and **6054**, are arranged on the downstream side, with respect to the mounting direction, of the developing containers **6051**, **6052**, **6053**, and **6054**. That is to say, the communication units **6051a**, **6052a**, **6053a**, and **6054a** are positioned on the side of the positioning pins **6588**. As mentioned above, the positioning pins **6588** position the main units of the developing containers **6051**, **6052**, **6053**, and **6054** with respect to the mounting and dismounting sections **6050a**, **6050b**, **6050c**, and **6050d**, so that on the downstream side, with respect to the mounting direction, of the developing containers **6051**, **6052**, **6053**, and **6054**, there is hardly any change in the distance between the main units of the developing containers **6051**, **6052**, **6053**, and **6054** and the printer main unit **6010a**. Moreover, even when there is a change in the relative position between the main units of the developing containers **6051**, **6052**, **6053**,

and **6054** and the coupling member **6590** provided on the upstream side with respect to the mounting direction, this has little influence at the downstream side in the mounting direction. For this reason, if the communication units **6051a**, **6052a**, **6053a**, and **6054a** are arranged on the downstream side, with respect to the mounting direction, of the main units of the developing containers **6051**, **6052**, **6053** and **6054**, that is, on the side of the positioning pins **588**, as in this embodiment, then is hardly any change in the distance between the printer main unit **6010a** and the communication units **6051a**, **6052a**, **6053a**, and **6054a** attached to the main units of the developing containers **6051**, **6052**, **6053**, and **6054**. Consequently, the communication units **6051a**, **6052a**, **6053a**, and **6054a** can communicate properly with the printer main unit **6010a**.

In this embodiment, the developing containers **6051**, **6052**, **6053**, and **6054** were explained to be cartridges, and as long as they are cartridges that can be mounted and dismounted to and from the printer main unit **6010a**, that are mounted by inserting them from one side of the printer main unit **6010a**, and that have communication units **6051a**, **6052a**, **6053a**, and **6054a**, it is possible to realize easy-to-mount cartridges by disposing the communication units **6051a**, **6052a**, **6053a**, and **6054a** on the downstream side with respect to the mounting direction, and arranging the non-contact IC chips **6051b**, **6052b**, **6053b**, and **6054b** within the communication units **6051a**, **6052a**, **6053a**, and **6054a** on the upstream side, with respect to the mounting direction, in the thin plate-shaped bases **6051i**, **6052i**, **6053i**, and **6054i**. For example, similar effects can also be attained when applying the communication unit **6075a** to the photoconductor unit **6075** including the photoconductor **6020**, as shown in FIG. 62.

Second Working Example

==Communication Distance and Communication Region of Communication Unit and Antenna Unit==

FIG. 80 is a cross-sectional view, taken from a direction perpendicular to the mounting direction, illustrating the communication distance and the communication region of the communication units and the antenna unit. FIG. 81 is a cross-sectional view, taken from a direction parallel to the mounting direction, illustrating the communication distance and the communication region of the communication units and the antenna unit.

As shown in these drawings, the communication units **6051a**, **6052a**, **6053a**, and **6054a** and the antenna unit **6124** are spaced apart by a communication distance **L**. The communication units **6051a**, **6052a**, **6053a**, and **6054a** are provided, respectively, on the developing containers **6051**, **6052**, **6053**, and **6054**. They are held by the developing container holding unit **6050** and are moved by rotating the developing container holding unit **6050** around its rotation shaft **6050e**. For this reason, the antenna unit **6124**, which is provided on the side of the printer main unit **6010a**, is arranged at a position where it does not come into contact with the portion protruding furthest outward when the developing container holding unit **6050** holding the developing containers **6051**, **6052**, **6053**, and **6054** rotates. On the other hand, rolls **6574** are provided on the axle sections **6510b** of the developing roller **6510** provided to the developing device, such that the developing roller **6510** and the photoconductor **6020** face each other at a predetermined distance. That is to say, the rolls **6574** are the only components that come in contact with the printer main unit **6010a**. For this reason, the communication units **6051a**, **6052a**, **6053a** and **6054a** are disposed inward

from the outer circumference of the rolls **6574**, that is, closer to the center of the rotation shaft **6050e**, and the antenna unit **6124** is disposed outward from the outer circumference of the rolls **6574**, that is, on the side that is further away from the center of the rotation shaft **6050e**.

The communication units **6051a**, **6052a**, **6053a**, and **6054a** and the antenna unit **6124** are arranged such that they face each other at the above-mentioned communication position, preferably spaced apart at a communication distance *L* of, for example, 10 mm, at which communication is possible. Moreover, the communication units **6051a**, **6052a**, **6053a**, and **6054a** do not include a power source, so that electric power is supplied to them through carrier waves from the antenna unit **6124**. That is to say, electric power supply as well as signals transmission to the communication units **6051a**, **6052a**, **6053a**, and **6054a** through electromagnetic induction occurring between the planar coil-shaped antennas **6054d** and **6124b** with which the communication units **6051a**, **6052a**, **6053a**, and **6054a** and the antenna unit **6124** are respectively provided. For this reason, when the communication units **6051a**, **6052a**, **6053a**, and **6054a** and the antenna unit **6124** communicate, a magnetic flux occurs around the copper foils of the antennas **6051d**, **6052d**, **6053d**, **6054d**, and **6124b**. This magnetic flux occurring at the antenna **6124b** of the antenna unit **6124** then has to reach the antennas **6051d**, **6052d**, **6053d**, and **6054d** of the communication units **6051a**, **6052a**, **6053a**, and **6054a**, which are removed by at least the communication distance *L*. That is to say, for the communication units **6051a**, **6052a**, **6053a**, and **6054a** and the antenna unit **6124** to communicate, it is necessary that magnetic flux can be generated in a region of the distance *L* around the copper foils of the antennas **6051d**, **6052d**, **6053d**, **6054d**, and **6124b** (referred to as "communication region M" below). It is preferable that the radius *L*, which defines the communication distance *L* and the communication region M, is set to such a distance that favorable communication conditions can be ensured, while considering the precision of the components of the communication units **6051a**, **6052a**, **6053a**, and **6054a** and the antenna unit **6124** or attachment errors when attaching components to the printer main unit **6010a**.

In the case of the present embodiment, around the communication units **6051a**, **6052a**, **6053a**, and **6054a** and the antenna unit **6124**, a region of the distance *L* from the center of the copper foil constituting the antennas of the communication units and the antenna of the antenna unit becomes the communication region M, as shown in FIG. 80 and FIG. 81.

Now, if there are conductive members within this communication region M, then the magnetic flux occurring in the antenna **6124b** passes through the conductive members, so that eddy currents flow through these conductive members with the magnetic flux at the axial center and the carrier wave is attenuated significantly. For this reason, the communication region M of the present embodiment is set to such a region that no other conductive members besides the communication units **6051a**, **6052a**, **6053a**, **6054a**, the antenna unit **6124** and the wires **6124e** are present within this communication region M. That is to say, conductive members such as the frame **6010f** and the stay **6010g** of the printer main unit **6010a**, the power source shielding member **6098a**, the cooling duct, and the metal components of the developing containers are all arranged outside the communication region M.

With the printer **6010** of the present embodiment, there are no conductive components other than the communication units **6051a**, **6052a**, **6053a**, **6054a**, the antenna unit **6124**, and the wires **6124e** connected to the antenna unit **6124** present within the communication region M, so that there are no conductive components hampering the communication

present in the communication region M of the communication units **6051a**, **6052a**, **6053a**, and **6054a** and the antenna unit **6124**. For this reason, a printer **6010** can be realized, with which favorable communication between the communication units **6051a**, **6052a**, **6053a**, **6054a** and the antenna unit **6124** is possible. Moreover, in the method for fixing the antenna unit **6124**, the antenna unit **6124** is accommodated in a holder **6125** made of resin and is held by engaging flexible tongues **6125b** provided on the holder **6125**, and the holder **6125** is fixed on the main unit side, so that it is possible to fix the antenna unit **6124** within the printer **6010** without disposing conductive components within the communication region M. That is to say, no metal holder and screws are used when fixing the antenna unit **6124**, so that there are no conductive components present within the communication region M. For this reason, favorable communication between the communication units **6051a**, **6052a**, **6053a**, **6054a** and the antenna unit **6124** is possible. Moreover, the tongues **6125b** engaging the antenna unit **6124** have flexibility, which also makes it easy to attach the antenna unit **6124** to the holder **6125**.

Moreover, in the printer of the present embodiment the metal shielding members, for example the frame **6010f** or the stay **6010g**, are outside of the communication region M, so that it is possible to let the communication units **6051a**, **6052a**, **6053a**, and **6054a** and the antenna unit **6124** communicate with favorable conditions. Furthermore, in the communication position, the power source unit **6098** is positioned at a spacing that is larger than the communication distance *L* on the opposite side of the developing containers **6051**, **6052**, **6053**, and **6054** with respect to the antenna unit **6124**, so that also the power source shielding member **6098a** functions as a shielding member when the communication units **6051a**, **6052a**, **6053a**, and **6054a** communicate with the antenna unit **6124** and it is possible to prevent the communication between the communication units **6051a**, **6052a**, **6053a**, and **6054a** and the antenna unit **6124** from being impeded by electromagnetic waves that are emitted from the power source unit **6098**.

In this embodiment, the developing containers **6051**, **6052**, **6053**, and **6054** were explained to be cartridges, and as long as they are cartridges that can be mounted and dismounted to and from the printer main unit **6010a**, and that have communication units **6051a**, **6052a**, **6053a**, and **6054a**, it is possible to realize a printer that allows communication under favorable conditions, through a configuration in which no conductive components other than the communication units **6051a**, **6052a**, **6053a**, and **6054a**, the antenna unit **6124**, and the wires **6124e** connected to the antenna unit **6124** are present within the communication region M. For example, similar effects can also be attained when providing the communication unit **6075a** on the photoconductor unit **6075** including the photoconductor **6020**, as shown in FIG. 62.

Other Embodiments

An image forming apparatus or the like according to the present invention was explained by way of the foregoing embodiment, but the foregoing embodiment of the invention is merely for the purpose of elucidating the present invention and is not to be interpreted as limiting the present invention. The invention can of course be altered and improved without departing from the gist thereof and equivalents are intended to be embraced therein.

In the foregoing embodiment, an intermediate image transfer type full-color laser beam printer was described as an example of the image forming apparatus, but the present invention can also be applied to various other types of image

forming apparatuses, such as full-color laser beam printers that are not of the intermediate image transfer type, monochrome laser beam printers, copying machines, and facsimiles.

Also, in the foregoing embodiment, the photoconductor, which is an image bearing member, was explained as having a photoconductive layer on the outer circumferential surface of a hollow cylindrical conductive member, but there is no limitation to this. For example, it may also be a so-called photoconductive belt, in which a photoconductive layer is provided on the surface of a belt-shaped photoconductive member.

Furthermore, in the foregoing embodiment, as shown in FIG. 63 for example, the mounting and dismounting sections 6050a, 6050b, 6050c, and 6050d are movable, and when the developing containers 6051, 6052, 6053, and 6054 are mounted to the mounting and dismounting sections and are moved to the developing position through the movement of the mounting and dismounting sections, then the latent image borne on the photoconductor 6020 (image bearing member) provided in the printer main unit 6010a is developed. Moreover, the communication units 6051a, 6052a, 6053a, and 6054a communicate in a noncontacting manner with the printer main unit 6010a when the developing containers 6051, 6052, 6053, and 6054 have been moved to the communication position, which is different from the developing position. However, there is no limitation to this. For example, it is also possible to let the developing containers not move at all.

However, if the developing containers 6051, 6052, 6053, and 6054 move together with the movement of the mounting and dismounting sections 6050a, 6050b, 6050c, and 6050d, then the relative position between the developing container main units and the coupling member 6590 changes more easily when the developing containers are positioned in the communication position than in the case that the developing containers do not move, so that there is a greater risk that the distance between the printer main unit 6010a and the communication units 6051a, 6052a, 6053a, and 6054a changes. Therefore, the effect of providing the communication units on the one end in the longitudinal direction of the developing container main units, that is, the effect that developing containers that can communicate properly with the printer main unit 6010a can be realized is more advantageous in the case that the developing containers move together with the movement of the mounting and dismounting sections. For this reason, the above-described embodiment is more preferable.

Furthermore, as shown in FIG. 65, in the foregoing embodiment, the mounting and dismounting sections 6050a, 6050b, 6050c, and 6050d are each provided with springs 6576, which bias the developing container main units in their longitudinal direction. Also, the relative position between the developing container main units and the coupling member 6590 is changed in accordance with the biasing amount of the springs 6576. However, there is no limitation to this. For example, it is also possible that the mounting and dismounting sections are not provided with springs biasing the developing container main units in their longitudinal direction.

However, if the mounting and dismounting sections 6050a, 6050b, 6050c, and 6050d are provided with springs 6576 that bias the developing container main units in their longitudinal direction, then the developing containers 6051, 6052, 6053, and 6054 oscillate due to the expansion and contraction of the springs 6576 when the developing containers are positioned in the communication position. Then, when the developing containers oscillate, there is the risk that the distance between the printer main unit 6010a and the communication units changes and that the communication units cannot communi-

cate properly with the printer main unit 6010a. Therefore, the effect of providing the communication units on the one end in the longitudinal direction of the developing container main units, that is, the effect that developing containers can be realized that can communicate properly with the printer main unit 6010a can be more effectively displayed in the case that the mounting and dismounting sections are provided with springs 6576. For this reason, the foregoing embodiment is more preferable.

Furthermore, in the foregoing embodiment, as shown in FIG. 70, the developing container main units include a developing roller 6510 (developer bearing member) for bearing toner T (developer) and developing the latent image borne on the photoconductor 6020 with toner T, and rolls 6574 (distance holding members) that are provided at both ends in the longitudinal direction of the developing rollers 6510 and that are for holding a distance between the photoconductor 6020 and the developing roller 6510 by coming into contact with the photoconductor 6020. Moreover, when the developing containers 6051, 6052, 6053, and 6054 are moved to the developing position, the rolls 6574 hold this distance by coming into contact with the photoconductor 6020. However, there is no limitation to this.

In order to properly develop the latent image carried on the photoconductor 6020, it is necessary to hold a proper distance between the developing roller 6510 and the photoconductor 6020. To hold this distance, rolls 6574 coming into contact with the photoconductor 6020 on both sides in longitudinal direction of the developing roller 6510 may be provided. In this case, if the relative position between the developing container main unit provided with the developing roller 6510 and the coupling member 6590 can change, the rolls 6574 can be contacted against the photoconductor 6020 such that the developing roller 6510 follows the photoconductor 6020 even if the photoconductor 6020 is attached at an inclination with respect to the printer main unit 6010a, so that it becomes possible to hold a proper distance between the developing roller 6510 and the photoconductor 6020. For this reason, the above-described embodiment is more preferable.

Furthermore, in the above-described embodiment, as shown in FIG. 68, the positioning member is a positioning pin 6588 (positioning shaft) that is fixed to the first side wall 6546 on one end in the longitudinal direction of the developing container main unit, such that its axial direction extends in the longitudinal direction of the developing container main unit. Moreover, as shown in FIG. 66, when the developing containers 6051, 6052, 6053, and 6054 are mounted to the mounting and dismounting sections 6050a, 6050b, 6050c, and 6050d, the positioning pins 6588 are fitted to the positioning holes 6058 provided on the mounting and dismounting sections to position the developing container main units with respect to the mounting and dismounting sections. However, there is no limitation to this. For example, it is also possible that the positioning member positions the developing container main units with respect to the mounting and dismounting sections with a configuration different from positioning pins 6588 fitted into positioning holes 6058.

However, if the positioning pins 6588 position the developing container main units with respect to the mounting and dismounting sections 6050a, 6050b, 6050c, and 6050d by fitting into positioning holes 6058, then the developing container main units can be positioned with respect to the mounting and dismounting sections with a simple configuration. For this reason, the above-described embodiment is more preferable.

Furthermore, as shown in FIG. 65, in the present embodiment, the mounting and dismounting sections 6050a, 6050b,

6050c, and **6050d** are each provided with coupling holes **6059**. Moreover, as shown in FIG. 72, the coupling member **6590** is provided with coupling pins **6595a** and **6595b** (coupling protrusions) that can be fitted into the coupling holes **6059**, and the coupling member **6590** is attached to the second side wall **6547** on the other end in longitudinal direction of the developing container main unit. Moreover, as shown in FIG. 66, when the developing containers **6051**, **6052**, **6053**, and **6054** are mounted to the mounting and dismounting sections **6050a**, **6050b**, **6050c**, and **6050d**, the coupling member **6590** is coupled to the mounting and dismounting section by fitting the coupling pins **6595a** and **6595b** into the coupling holes **6059**. However, there is no limitation to this. For example, it is also possible to couple the coupling member **6590** with the mounting and dismounting section with another configuration than coupling the coupling pin **6595a** into the coupling hole **6059**.

However, if the coupling member **6590** is coupled with the mounting and dismounting sections **6050a**, **6050b**, **6050c**, and **6050d** by fitting the coupling pins **6595a** and **6595b** into the coupling holes **6059**, then it is possible to couple the coupling member **6590** with the mounting and dismounting sections with a simple configuration. For this reason, the above-described embodiment is more preferable.

Furthermore, as shown in FIG. 71, in the foregoing embodiment, the developing container main units are provided with attachment protrusions **6581a** and **6581b** having a circular cross section. Moreover, the coupling member **6590** is provided with attachment holes (**6593a** into which the attachment protrusion **6581a** can be fitted and **6593b** into which the attachment protrusion **6581b** can be fitted) which have an elliptical cross section and into which attachment protrusions can be fitted. Moreover, the attachment holes **6593a** and **6593b** allow some movement of the attachment protrusions fitted into those attachment holes within the attachment holes. However, there is no limitation to this. For example, it is also possible that the cross-sectional shape of the attachment holes **6593a** and **6593b** is a shape other than a substantially elliptical shape.

Furthermore, in the foregoing embodiment, as shown in FIG. 68, the developing container main unit is supported by the housing **6540** at both ends in the longitudinal direction, and is provided with the developing roller **6510** for bearing the toner **T** and developing the latent image borne on the photoconductor **6020** with the toner **T**. Moreover, as shown in FIG. 69, the outer surface **6543** of the housing **6540** is provided with a circularly arc-shaped surface **6543a**, whose cross section through a perpendicular plane that is perpendicular to the longitudinal direction of the housing **6540** is circularly arc-shaped. And as shown in FIG. 69, the communication units **6051a**, **6052a**, **6053a**, and **6054a** are attached at positions of the circularly arc-shaped surface **6543a** that are furthest removed from the developing rollers **6510**. However, there is no limitation to this. For example, it is also possible that the communication units are attached at positions of the circularly arc-shaped surface **6543a** that are close to the developing rollers **6510**.

However, if the communication units **6051a**, **6052a**, **6053a**, and **6054a** are attached at the positions of the circularly arc-shaped surface **6543a** that are furthest removed from the developing rollers **6510**, then it can be prevented that the toner **T** borne on the developing roller **6510** is scattered and adheres to the communication units, so that the communication units can communicate more properly with the printer main unit **6010a**. For this reason, the above-described embodiment is more preferable.

====Configuration of Image Forming System Etc.====

Next, an embodiment of an image forming system serving as an example of an embodiment of the present invention is described with reference to the drawings.

- 5 FIG. 82 is an explanatory diagram showing the external configuration of an image forming system. An image forming system **6700** is provided with a computer **6702**, a display device **6704**, a printer **6010**, input devices **6708**, and reading devices **6710**.
- 10 In this embodiment, the computer **6702** is contained within a mini-tower type housing, but there is no limitation to this. A CRT (cathode ray tube), plasma display, or liquid crystal display device, for example, is generally used as the display device **6704**, but there is no limitation to this. As the printer **6010**, the printer described above is used. In this embodiment, the input devices **6708** are a keyboard **6708A** and a mouse **6708B**, but there is no limitation to these. In this embodiment, a flexible disk drive device **6710A** and a CD-ROM drive device **6710B** are used as the reading devices **6710**, but there
- 15 is no limitation to these, and they may also include an MO (magneto-optical) disk drive device or a DVD (digital versatile disk), for example.

- 20 FIG. 83 is a block diagram showing the configuration of the image forming system shown in FIG. 82. An internal memory **6802** such as a RAM is provided within the casing containing the computer **6702**, and furthermore an external memory such as a hard disk drive unit **6804** is provided.

- 25 In the above explanations, an example was given in which the image forming system is constituted by connecting the printer **6010** to the computer **6702**, the display device **6704**, the input device **6708**, and the reading device **6710**, but there is no limitation to this. For example, the image forming system may also be made of the computer **6702** and the printer **6010**, and the image forming system does not have to be provided with any one of the display device **6704**, the input device **6708**, and the reading device **6710**.

- 30 It is also possible that the printer **6010** has some of the functions or mechanisms of each of the computer **6702**, the display device **6704**, the input device **6708**, and the reading device **6710**. For example, the printer **6010** may be configured so as to have an image processing section for carrying out image processing, a display section for carrying out various types of displays, and a recording media mounting and dismounting section into and from which recording media storing image data captured by a digital camera or the like are inserted and taken out.

- 35 As an overall system, the image forming system that is thus achieved is superior to conventional systems.

50 Overview of Image Forming Apparatus of Eighth Embodiment

Referring to FIGS. 84 to 89, an overview of a laser beam printer (hereinafter, also referred to as "printer") **7010** serving as an example of an image forming apparatus is described. FIG. 84 is a diagram illustrating the configuration of a printer main unit **7010a** with respect to which developing containers **7051**, **7052**, **7053**, and **7054** can be mounted and dismounted. FIG. 85 is a diagram showing the main structural components 55 constituting the printer **7010**. FIG. 86 is a block diagram showing the control unit **7100** of the printer **7010**. FIG. 87 is a perspective view of a developing container holding unit **7050**. FIG. 88 is a diagram showing the developing container holding unit **7050** in a state in which a yellow developing container **7054** is mounted to a mounting and dismounting section **7050d**. FIG. 89 is a diagram showing the positions of the mounted developing container and the developing con-

tainer holding unit. It should be noted that FIG. 85 is a diagram of a cross section taken perpendicular to the mounting direction of the developing container, for example, in FIG. 84. Also, the vertical direction is indicated by arrows in FIG. 84 and FIG. 85, and for example, a paper supply tray 7092 is disposed at a lower part of the printer 7010 and a fixing unit 7090 is disposed at an upper part of the printer 7010.

<Mounting and Dismounting Configuration>

Developing containers 7051, 7052, 7053, and 7054, which are examples of developing devices, and a photoconductor unit 7075 can be mounted to and dismounted from a printer main unit 7010a, which is an example of an image forming apparatus main unit. The printer 7010 is configured by mounting the developing containers 7051, 7052, 7053, and 7054 and the photoconductor unit 7075 to the printer main unit 7010a.

The printer main unit 7010a has a first opening cover 7010b that can be opened and closed, a second opening cover 7010c that can be opened and closed and that is provided further inward than the first opening cover 7010b, a photoconductor unit mounting and dismounting opening 7010d through which the photoconductor unit 7075 can be mounted and dismounted, and a developing container mounting and dismounting opening 7010e serving as an opening through which the developing containers 7051, 7052, 7053, and 7054 can be mounted and dismounted.

Here, by opening the first opening cover 7010b, the user can mount and dismount the photoconductor unit 7075, which is devised as a cartridge, with respect to the printer main unit 7010a through the photoconductor unit mounting and dismounting opening 7010d. Further, by opening the second opening cover 7010c, the user can mount and dismount the developing containers 7051, 7052, 7053, and 7054, which are devised as cartridges, with respect to the printer main unit 7010a through the developing container mounting and dismounting opening 7010e.

<Configuration of the Printer 7010>

The configuration of the printer 7010 in a state in which the developing containers 7051, 7052, 7053, and 7054 and the photoconductor unit 75 are mounted to the printer main unit 7010a is described.

As shown in FIG. 85, the printer 7010 according to this embodiment includes a charging unit 7030, an exposing unit 7040, a developing container holding unit 7050, an image transfer unit 7060, a decharging unit 7070, and a cleaning blade 7076. These units are arranged along the rotation direction of a photoconductor 7020, which is an example of an image bearing member bearing a latent image. The printer 7010 further includes a fixing unit 7090, a display unit 7095 constituted by a liquid-crystal panel and serving as a means for giving notifications to the user, a control unit 7100 (see FIG. 86) for controlling these units and managing the operations of the printer, and a power source unit 7098 covered by a power source shielding member 7098a.

The photoconductor 7020 has a hollow cylindrical conductive base and a photoconductive layer formed on the outer circumferential surface of the conductive base, and is rotatable around its center axis. In the present embodiment, the photoconductor 7020 rotates clockwise, as indicated by the arrow in FIG. 86. The charging unit 7030 is a device for charging the photoconductor 7020. In the present embodiment, the photoconductor 7020, the cleaning blade 7076, and the charging unit 7030 are configured as one photoconductor unit 7075 provided with a waster toner container.

The exposing unit 7040 is a device for forming a latent image on the photoconductor 7020, which has been charged

by irradiating a laser beam on the photoconductor 7020. The exposing unit 7040 includes, for example, a semiconductor laser, a polygon mirror, and an F-θ lens, and irradiates a modulated laser beam onto the charged photoconductor 7020 in accordance with image signals that have been input from a host computer, not shown in the drawings, such as a personal computer or a word processor.

The developing container holding unit 7050 is a device for developing the latent image formed on the photoconductor 7020 using toner T, which is an example of a developer contained in developing containers 7051, 7052, 7053, and 7054, that is, black (K) toner contained in a black developing container 7051, magenta (M) toner contained in a magenta developing container 7052, cyan (C) toner contained in a cyan developing container 7053, and yellow (Y) toner contained in a yellow developing container 7054.

This developing container holding unit 7050 includes a rotation shaft 7050e and four mounting and dismounting sections 7050a, 7050b, 7050c, and 7050d with respect to which the developing containers 7051, 7052, 7053, and 7054 can be mounted and dismounted and which are disposed at intervals of 90° in circumferential direction around the rotation shaft. The mounting and dismounting sections 7050a, 7050b, 7050c, and 7050d are moved by rotating the developing container holding unit 7050 around the rotation shaft 7050e.

Each of the mounting and dismounting sections 7050a, 7050b, 7050c, and 7050d is provided with the same space, partitioned by two neighboring wall sections 7050f of the four wall sections 7050f formed at intervals of 90° in four radial directions from the rotation shaft 7050e provided in the middle of the developing container holding unit 7050. That is to say, the mounting and dismounting section 7050a with respect to which the black developing container 7051 can be mounted and dismounted, the mounting and dismounting section 7050b with respect to which the magenta developing container 7052 can be mounted and dismounted, the mounting and dismounting section 7050c with respect to which the cyan developing container 7053 can be mounted and dismounted, and the mounting and dismounting section 7050d with respect to which the yellow developing container 7054 can be mounted and dismounted are disposed at intervals of 90° in circumferential direction around the rotation shaft 7050e in the developing container holding unit 7050.

In this embodiment, the positions of the four developing containers 7051, 7052, 7053, and 7054 can be moved by shifting the mounting and dismounting sections 7050a, 7050b, 7050c, and 7050d. That is to say, the four developing containers 7051, 7052, 7053, and 7054 can be rotated around the rotation shaft 7050e while maintaining their relative positions. Then, when the developing containers 7051, 7052, 7053, and 7054 are mounted to the mounting and dismounting sections 7050a, 7050b, 7050c, and 7050d and are moved to the developing position through the movement of the mounting and dismounting sections 7050a, 7050b, 7050c, and 7050d, the latent image borne by the photoconductor 7020 is developed with the toner contained in the respective developing containers 7051, 7052, 7053, and 7054 together with a carrier. It should be noted that details of the developing containers are discussed later.

As shown in FIG. 87, the mounting and dismounting sections 7050a, 7050b, 7050c, and 7050d are each provided with coupling holes 7059 into which coupling protrusions (not shown in the drawings) provided on the upstream side of the developing containers can be fitted, guiding sections 7056 for guiding the developing containers by engaging with a guided section 7549 provided on the developing containers that are

151

inserted from the developing container mounting and dismounting opening **7010e**, and springs **7576** for biasing the developing containers toward the outer circumferential direction of the developing container holding unit **7050**.

And as shown in FIG. 89, the guiding sections **7056** are provided on each of the two wall sections **7050f** constituting the mounting and dismounting section. The guiding sections **7056** have perpendicular surfaces formed on the two wall sections **7050f** and are arranged extending along the longitudinal direction of the yellow developing container **7054**, protruding on the side of the same space partitioned by the two adjacent wall sections **7050f**. That is to say, the guiding sections **7056**, which are provided on adjacent wall sections **7050f** facing toward the same space, are formed such that their surfaces both face toward the rotation shaft **7050e** and their surfaces define an angle of substantially 90°. The yellow developing container **7054** is mounted by arranging the guided sections **7549** of the yellow developing container **7054** such that they are on the side of the rotation shaft **7050e** with respect to the two perpendicular surfaces of the guiding sections **7056**, and inserting the guided sections **7549** along the guiding sections **7056**.

The springs **7576** provided on the mounting and dismounting section **7050d** bias the yellow developing container **7054** toward the outer circumferential direction of the developing container holding unit **7050**. Thus, when the yellow developing container **7054** is inserted from the developing container mounting and dismounting opening **7010e** with the guided sections **7549** being arranged on the side of the rotation shaft **7050e** with respect to the perpendicular surfaces of the guiding sections **7056**, the yellow developing container **7054** is biased by the springs **7576** toward the outer circumferential direction.

Then, positioning pins (not shown in the drawings) respectively provided on the downstream side of the developing containers fit into corresponding positioning holes **7058** shown in FIG. 87, and the yellow developing container **7054** is positioned in its predetermined position and mounted by fitting a coupling protrusion provided on the upstream side of the yellow developing container **7054** into a coupling hole **7059** provided on the mounting and dismounting section **7050d**, as shown in FIG. 88.

The image transfer unit **7060** includes an image transfer drum **7061** made of a dielectric film that is provided in opposition to the photoconductor **7020** and is for electrostatically adsorbing paper serving as the medium to be carried, and a transfer corotron **7062** that is disposed inside the image transfer drum **7061** and is for applying to the paper a charge of a polarity that is opposite to that of the toner from the rear side of the adsorbed paper. That is to say, the carried paper is electrostatically adsorbed to the image transfer drum **7061**, and at the position opposite to the developing roller **7510**, the monochrome toner image formed on the photoconductor **7020** is transferred to the paper. Then, when the four toner images have been successively transferred, a full-color toner image is formed on the paper. This image transfer drum **61** is rotatively driven at substantially the same speed as the photoconductor **7020**.

The fixing unit **7090** is a device for fusing the single-color toner image or the full-color toner image, which has been formed on the paper, and to turn it into a permanent image.

The discharging unit **7070** is a device for removing the electrical potential of the photoconductor **7020** after the image transfer. The cleaning blade **7076** is made of rubber and is in contact with the surface of the photoconductor **7020**. The cleaning blade **7076** scrapes off and removes toner remaining

152

on the photoconductor **7020**, after the toner image has been transferred onto the paper by the image transfer unit **7060**.

The photoconductor unit **7075** is provided between the image transfer unit **7060** and the exposing unit **7040**, and includes the photoconductor **7020**, the discharging unit **7070**, the cleaning blade **7076**, and a waste toner container not shown in the drawings containing toner that has been scraped away by the cleaning blade **7076**.

10 The control unit **7100** is made of a main controller **7101** and a unit controller **7102**, as shown in FIG. 86. An image signal is input into the main controller **7101**, and in accordance with a command based on this image signal, the unit controller **7102** controls the various units, for example, to form the image.

<Operation of the Printer **7010**>

The operation of the printer **7010** configured as above is described below, referring to other structural components thereof as well.

20 First, when an image signal from a host computer not shown in the drawings is input into the main controller **7101** of the printer **7010** via an interface (I/F) **7112**, the photoconductor **7020**, the developing rollers **7510** provided in the developing containers **7051**, **7052**, **7053**, and **7054**, and the image transfer drum are rotated under the control of the unit controller **7102** based on a command from the main controller **7101**. While rotating, the photoconductor **7020** is successively charged by the charging unit **7030** at a charging position.

25 The region of the photoconductor **7020** that has been charged is brought to an exposure position through rotation of the photoconductor **7020**, and a latent image corresponding to image information of a first color, for example yellow Y, is formed at that region by the exposing unit **7040**. Moreover, the developing container holding unit **7050** positions the yellow developing container **7054** containing the yellow (Y) toner at the developing position opposite the photoconductor **7020**.

30 The latent image formed on the photoconductor **7020** is brought to a developing position through the rotation of the photoconductor **7020**, and is developed with yellow toner by the yellow developing container **7054**. Thus, a yellow toner image is formed on the photoconductor **7020**. The yellow toner image that is formed on the photoconductor **7020** is brought to the image transfer position through rotation of the photoconductor **7020** and is transferred to paper by the image transfer unit **7060**.

35 The above process is repeated for a second color, a third color, and a fourth color, thereby transferring toner images of four colors corresponding to various image signals layered over one another onto the paper. Thus, a full color toner image is formed on the paper.

40 The full-color toner image formed on the paper is moved by rotating the image transfer drum **7061**. Then, the paper is stripped off the image transfer drum **7061** by a wedge-shaped stripping tongue **7063** whose front end contacts against the image transfer drum **7061**, and carried towards the fixing unit **7090**.

45 The full-color toner image on the paper that has reached the fixing unit **7090** is turned into a permanent image by fusing it through the application of heat and pressure with the fixing unit **7090**. On the other hand, after the photoconductor **7020** has passed the image transfer unit **7060** and after the charge has been removed by the discharging unit **7070**, the toner adhering to its surface is scraped off by the cleaning blade

153

7076 and it is provided with a charge for forming the next latent image. The toner that is scraped off is collected in the waste toner container.

====Overview of the Control Unit====

The configuration of the control unit 7100 is described next, with reference to FIG. 86. The control unit 7100 includes the main controller 7101 and the unit controller 7102.

The main controller 7101 includes a CPU 7111, an interface 7112 for connection to a computer not shown in the drawings, an image memory 7113 for storing image signals input from the computer, and a main controller-side memory 7114 made of an EEPROM 7114a that can be rewritten electrically, a RAM 7114b, and a program ROM or the like in which a program for the various kinds of control is stored.

The CPU 7111 of the main controller 7101 controls the reading in and the reading out of image data that has been input via the interface into the image memory 7113, and performs the control of the overall apparatus in synchronization with the CPU 7120 of the unit controller 7102 based on the control signals input from the computer.

The unit controller 7102 includes the CPU 7120, a unit controller-side memory 7116 including an EEPROM 7116a that can be rewritten electrically, a RAM, and a program ROM or the like in which a program for the various kinds of control is stored, as well as drive control circuits or the like for performing drive control of the various units of the entire device (the charging unit 7030, the exposing unit 7040, the developing container holding unit 7050, the image transfer unit 7060, the photoconductor unit 7075, the decharging unit 7070, the fixing unit 7090, and the display unit 7095).

The CPU 7120 of the unit controller 7102 is electrically connected to the various drive control circuits and controls the various drive control circuits in accordance with control signals from the CPU 7111 of the main controller 7101. That is to say, while the state of the units is detected by receiving signals from sensors or the like provided in each of the units, the units are controlled in accordance with signals input from the main controller 7101.

Also, the CPU 7120 provided in the unit controller 7102 is connected to a non-volatile storage element (hereinafter, also referred to as "main unit-side memory") 7122 such as a serial EEPROM via the serial interface (I/F) 7121. This main unit-side memory 7122 stores data that is necessary for the control of the apparatus.

Furthermore, the CPU 7120 is capable of wirelessly communicating with communication units 7051a, 7052a, 7053a, and 7054a, which are respectively provided on the developing containers 7051, 7052, 7053, and 7054, via the serial interface 7121, a communication control module 7123 and an antenna unit 7124 serving as a main unit-side antenna. Through the communication of the antenna unit 7124 and the communication units 7051a, 7052a, 7053a, and 7054a, the control unit 7100 can write information into the communication units 7051a, 7052a, 7053a, and 7054a provided in the developing containers 7051, 7052, 7053, and 7054 as well as read in information from the communication units 7051a, 7052a, 7053a, and 7054a provided in the developing containers 7051, 7052, 7053, and 7054. The communication units 7051a, 7052a, 7053a, and 7054a are explained further below.

====Overview of the Developing Containers====

A developer D, which is used in the printer 7010 of this embodiment, is a two-component developer in which a non-magnetic toner is mixed with a magnetic carrier. The developing containers 7051, 7052, 7053, and 7054 mix and stir this developer in their interior and the latent image written onto

154

the photoconductor 7020 is developed by the so-called magnetic brush developing method.

The configuration and operation of the developing containers 7051, 7052, 7053 and 7054 is explained with reference to FIG. 90. FIG. 90 is a cross-sectional view showing the main structural components of the yellow developing container 7054. In FIG. 90, as in FIG. 84, the vertical direction is indicated by arrows. Also, in FIG. 90, the yellow developing container 7054 is shown positioned at a developing position 10 that is in opposition to the photoconductor 7020.

The black developing container 7051 containing black (K) toner, the magenta developing container 7052 containing magenta (M) toner, the cyan developing container 7053 containing cyan (C) toner, and the yellow developing container 15 7054 containing yellow (Y) toner can be mounted to the developing container holding unit 7050, but since the configuration and the operation of each of the developing containers is the same, explanations are given only for the yellow developing container 7054 in the following.

20 <Internal Configuration of the Yellow Developing Container 7054>

First, the configuration of the yellow developing container 7054 is described. The yellow developing container 7054 includes a developing roller 7510, which is an example of a developer carrying member, a regulating blade 7560, a housing 7540 serving as a developer containing section forming a first developer containing section 7530 and a second developer containing section 7531, and augers 7520 and 7521 for carrying the developer while stirring it within the first developer containing section 7530 and the second developer containing section 7531.

25 The developing roller 77510 bears toner T and carries it to the developing position opposite the photoconductor 7020, and develops the latent image borne by the photoconductor 7020 with the toner T carried to the developing position. This developing roller 77510 includes a magnet roller with a plurality of magnetic poles, and a hollow cylindrical sleeve that rotates while covering the circumference of the magnet roller. 30 By adsorbing polarized carriers in lines to the circumferential surface of the sleeve due to the magnetic force of the magnet roller, the developer D is held in the form of spikes, thus forming a so-called magnetic brush. Then, the developer D of this magnetic brush is carried with the rotation of the sleeve to the outside through a housing opening 7572 provided in the housing 7540, and the grains of developer D standing on the magnetic brush are rubbed onto the photoconductor 7020.

35 Inside the housing 7540, the regulating blade 7560 is disposed at a predetermined spacing to the developing roller 7510. The length of the spikes of the magnetic brush formed 40 on the circumferential surface of the developing roller 7510 is adjusted to a predetermined length by the regulating blade 7560.

45 The housing 7540 is fabricated by welding together a plurality of integrally molded housing sections, namely an upper housing section 7542 and a lower housing section 7544. A communication unit 7054a is attached to an outer circumferential portion of the housing 7540. The housing 7540 has a housing opening 7572 at its bottom, and is arranged such that 50 a portion of the developing roller 7510 is exposed in this housing opening 7572, as mentioned above.

55 The inside of the housing 7540 includes an intrusion prevention section 7546 for preventing the developer from intruding to a predetermined region by partitioning the interior side of the position where the communication unit 7054a is arranged from other regions. This intrusion prevention section 7546 is formed by a partitioning member 7546a that

155

provides a partition so that the developer cannot intrude to the side of the inner surface where the communication unit **7054a** is provided. A gap is formed by the interior that is enclosed by the partitioning member **7546a** and the housing **7540**.

Parallel to the axial direction of the developing roller **7510**, the housing **7540** is provided with a partitioning wall **7545** that protrudes inward from an inner wall (in vertical direction in FIG. 90). Except for the region that is partitioned by the partitioning member **7546a**, the space inside the housing **7540** is divided into two developer containing sections, namely the first developer containing section **7530** and the second developer containing section **7531**. The partitioning wall **7545** is provided with respective connection openings (not shown in the drawings) on the upstream side and the downstream side in the mounting direction, and the first developer containing section **7530** and the second developer containing section **7531** are connected by these connection openings.

Moreover, the first auger **7520**, which is formed with a screw shape adjacent to the developing roller **7510**, is arranged in the first developer containing section **7530**, which includes the developing roller **7510**. By rotating in the direction of the arrow in FIG. 7, this first auger **7520** carries the developer D within the first developer containing section **7530** towards the upstream side (the side to the front in a direction perpendicular to the paper plane) with respect to the mounting direction of the developing container **7054**. On the other hand, a second auger **7521**, that is substantially the same as the first auger **7520**, is arranged in the second developer containing section **7531**, which is adjacent to the first developer containing section **7530** with the partitioning wall **7545** arranged between them. By rotating in the direction of the arrow in FIG. 90, this second auger **7521** carries the developer D inside the second developer containing section **7531** towards the downstream side (the side behind in a direction perpendicular to the paper plane) with respect to the mounting direction of the developing container **7054**.

The first developer containing section **7530** and the second developer containing section **7531** are connected through the connection openings, so that the developer D that has been carried to the upstream side within the first developer containing section **7530** due to the rotation of the first auger **7520** is moved through the connection opening on the upstream side to the second developer containing section **7531**. On the other hand, the developer D that has been carried to the downstream side within the second developer containing section **7531** due to the rotation of the second auger **7521** is moved through the connection opening on the downstream side to the first developer containing section **7530**. That is to say, when the pair of first and second augers **7520** and **7521** is rotated by the developing containers **7051**, **7052**, **7053**, and **7054**, the developer D is circulated in a constant direction around the partitioning wall **7545**, and this circulation not only stirs the developer D, but also enhances the frictional electrification of the toner.

—The Developing Position, Communication Position and Mounting and Dismounting Position of the Developing Containers—

As mentioned above, the developing containers **7051**, **7052**, **7053**, and **7054** are moved together with the movement of the mounting and dismounting sections **7050a**, **7050b**, **7050c**, and **7050d**. At that time, the mounting and dismounting sections are moved such that the developing containers are positioned in predetermined positions. Such predetermined positions are the developing position, serving as a first position, the communication position, serving as a second

156

position, and the mounting and dismounting position. Since the developing position, the communication position, and the mounting and dismounting position of each of the developing containers are the same, the developing position, the communication position, and the mounting and dismounting position of the yellow developing container **7054** are explained in the following with reference to FIGS. 91A to 91D. FIG. 91A is a diagram showing the developing container holding unit **7050** in a state where the yellow developing container **7054** is positioned at the developing position. FIG. 91B is a diagram showing the developing container holding unit **7050** in a state where the yellow developing container **7054** is positioned at the communication position. FIG. 91C is a diagram showing the developing container holding unit **7050** in a state where the yellow developing container **7054** is positioned at the mounting and dismounting position. FIG. 91D is a diagram showing a state where the developing container holding unit **7050** is positioned in its home position.

In the state shown in FIG. 91A, the yellow developing container **7054** is positioned at the developing position in which the developing roller **7510** is in opposition to the photoconductor **7020**. In this state, the developing roller **7510** forming the magnetic brush rubs against the photoconductor **7020** with the spikes of the magnetic brush, so that the latent image borne on the photoconductor **7020** can be developed. In the state in which the yellow developing container **7054** is positioned in the developing position, as noted above, the springs **7576** provided in the mounting and dismounting section **7050d** bias the yellow developing container main unit towards the outer circumferential side. It should be noted that in a state in which the yellow developing container **7054** is positioned in the developing position, the magenta developing container **7052** is positioned in the communication position.

Furthermore, when the developing container holding unit **7050** is rotated for a predetermined angle in Z-direction in FIG. 91A from the state shown in FIG. 91A around its rotation shaft **7050e**, then the state shown in FIG. 91B is achieved. In the state shown in FIG. 91B, the yellow developing container **7054** is positioned in the communication position. In this state, the communication unit **7054a** provided on the yellow developing container **7054** opposes the antenna unit **7124** in a noncontacting manner. This communication unit **7054a** can then communicate with the antenna unit **7124**. It should be noted that when the yellow developing container **7054** is positioned in the communication position, the black developing container **7051** is positioned in the developing position. Therefore, the communication between the antenna unit **7124** and the communication unit can take place while the black developing container **7051** develops the latent image borne on the photoconductor **7020**.

Furthermore, when the developing container holding unit **7050** is rotated around its rotation shaft **7050e** for a predetermined angle in Z-direction in FIG. 91B from the state shown in FIG. 91B, then the state shown in FIG. 91C is achieved. In the state shown in FIG. 91C, the yellow developing container **7054** is positioned in the mounting and dismounting position. In this state, the yellow developing container **7054** can be mounted and dismounted via the developing container mounting and dismounting opening **7010e**, that is, the yellow developing container **7054** can be mounted to the mounting and dismounting section **7050d** or it can be dismounted from the mounting and dismounting section **7050d**.

It should be noted that after the power source of the printer main unit **7010a** has been turned on and an initialization operation has been performed, and before the printer **7010**

forms an image, the developing container holding unit 7050 is positioned in the home position shown in FIG. 91D.

====Configuration of the Communication Units=====

The configuration of the communication units provided in the developing containers as well as the configuration for sending and receiving data is described next with reference to FIG. 92, FIG. 93, and FIG. 94. FIG. 92 is a plan view showing the configuration of a communication unit. FIG. 93 is a block diagram illustrating the internal configuration of the communication unit and the send/receive section. FIG. 94 is a diagram illustrating the information stored in a memory cell 7054h of the communication unit 7054a.

Communication units are attached respectively to the developing containers 7051, 7052, 7053, and 7054, but since the configuration of the communication units attached to the developing containers and the positions at which the communication units are attached to the developing containers are the same for all developing containers, the following is an explanation taking the communication unit 7054a attached to the yellow developing container 7054 as an example.

When the yellow developing container 7054 is mounted to the mounting and dismounting section 7050d, the communication unit 7054a can communicate with the antenna unit 7124 on the side of the printer main unit 7010a in a noncontacting manner. As mentioned above, the yellow developing container 7054 is moved by the movement of the mounting and dismounting section 7050d. When the yellow developing container 7054 has been moved to the communication position, which is different from the developing position, the communication unit 7054a communicates in a noncontacting manner with the antenna unit 7124 with which the printer main unit 7010a is provided. The communication unit 7054a is provided inward of the antenna unit 7124 in radial direction with respect to the center of the rotation shaft 7050e of the developing container holding unit 7050.

The communication unit 7054a includes a thin plate-shaped substrate 7054i serving as a substrate made of a thin plate-shaped piece of plastic that is flexible in its longitudinal direction, an antenna 7054d serving as a container-side antenna made by arranging copper foil in a rectangular planar coil shape, antenna terminals 7054j provided on both ends of the antenna, a non-contact IC chip 7054b including a memory and serving as an element for communicating with an external antenna, two coupling sections 7054k made of aluminum that connect the chip terminals of the non-contact IC chip 7054b with the antenna terminals 7054j, and a film-shaped protective sheet 7054m covering these elements, and sandwiching them together with the thin plate-shaped substrate 7054i.

As shown in FIG. 92, one antenna terminal 7054j of the antenna 7054d is arranged at one end in the longitudinal direction of the rectangular thin plate-shaped substrate 7054i, the antenna 7054d is wrapped about ten times in a coil shape along the outer shape of the thin plate-shaped substrate 7054i, and the other antenna terminal 7054j is provided to the inner side of the antenna 7054d. The outer antenna terminal 7054j and the inner antenna terminal 7054j are both provided on the same side in the longitudinal direction of the thin plate-shaped substrate 7054i. On the thin plate-shaped substrate 7054i, the ten copper foil structures of the antenna 7054d are lined up next to each other along the vertical and horizontal edges of the rectangular shape, and are divided into five each on that side of the thin plate-shaped substrate 7054i where the antenna terminals 7054j are provided, the non-contact IC chip 7054b being arranged between these. Furthermore, two coupling sections 7054k connecting chip terminals (not shown in the drawings) provided on the non-contact IC chip 7054b

with the antenna terminals 7054j are provided, respectively straddling five copper foil structures. That is to say, on the thin plate-shaped substrate 7054i, the non-contact IC chip 7054b, two antenna terminals 7054j, and two coupling sections 7054k are provided on one end in longitudinal direction, and the copper foil structures serving as the antenna 7054d are guided around the remaining region, except for the center.

The communication unit 7054a is positioned downstream with respect to the mounting direction of the yellow developing container 7054, in the longitudinal direction of the yellow developing container main unit. In this situation, the communication unit 7054a is arranged such that the end where the non-contact IC chip 7054b is provided is arranged on the upstream side of the communication unit 7054a with respect to the mounting direction.

Moreover, the communication unit 7054a is attached to an outer surface 7543 of the housing 70540, which is provided extending in the longitudinal direction of the housing 70540. Here, the outer surface 7543 refers to the part of the housing 70540 corresponding to the dash-dotted line in FIG. 90. It should be noted that this outer surface 7543 includes a circularly arc-shaped surface 7543a, whose cross section through a perpendicular plane that is perpendicular to the longitudinal direction of the housing 70540 is circularly arc-shaped. This circularly arc-shaped surface 7543a is arranged such that its circular arc extends along the rotation direction of the developing container holding unit 7050 when the yellow developing container 7054 is mounted to the mounting and dismounting section 7050d. As shown in FIG. 90, the communication unit 7054a is attached at a position of the circularly arc-shaped surface 7543a that is furthest removed from the developing roller 7510.

FIG. 95 is a diagram illustrating the antenna unit 7124. FIG. 96 is a diagram illustrating how the antenna unit is attached to a holder. The antenna unit 7124 provided on the side of the printer main unit 7010a includes a substrate 7124a that is formed on a plate material made of resin, an antenna 7124b serving as a main unit-side antenna that is made of copper foil wrapped in a planar coil shape along the outer shape of the substrate 7124a, substantially as in the communication unit 7054a, antenna terminals 7124c provided at the ends of the antenna 7124b, and a film-shaped protective sheet 7124d. Furthermore, the two antenna terminals 7124c are each connected to a wire 7124e and connected to the control unit 7100 via the communication control module 7123. Here, the antenna unit 7124 of the present embodiment is configured having a protective sheet 7124d, but it is not necessarily required to provide the protective sheet 7124d.

When the mounted yellow developing container 7054 has been arranged in the communication position, the antenna 7054d of the communication unit 7054a and the antenna 7124b of the antenna unit 7124 are arranged at positions facing each other. Moreover, the antenna unit 7124 is fixed via a holder 7125 made of resin to the printer main unit 7010a.

The holder 7125 is box-shaped, covering the surroundings of the antenna unit 7124 as well as the sides of the substrate 7124a and open on one side, and is arranged such that the antenna 7124b faces the outside from the open side. At the edges of the open side of the holder 7125, flexible tongues 7125b protruding toward the inside are provided on opposing side walls 7125a. The antenna unit 7124 is accommodated inside the box-shaped holder 7125 and is held there by the tongues 7125b. That is to say, the antenna unit 7124 is held only by the holder 7125 made of resin, so that metal components such as screws are not required to fasten the antenna unit 7124.

159

If the communication unit **7054a** and the antenna unit **7124** are in a predetermined positional relationship, for example, if they are within a distance of 10 mm of one another, then information can be exchanged in a noncontacting manner between the two. The communication unit **7054a** is overall very compact and thin, and one of its sides is adhesive and can be adhered to an object as a seal. It is also called a memory tag, for example, and is commercially available in various forms.

As shown in FIG. 93, the non-contact IC chip **7054b** includes a resonance capacitor **7054c**, a rectifier **7054e**, a signal analysis section RF (Radio Frequency) **7054f**, a controller **7054g**, and the memory cell **7054h**. The memory cell **7054h** is a non-volatile memory that can be electrically read and written, such as an NAND flash ROM, and is capable of storing information that has been written on it and reading stored information from the outside.

The antenna **7054d** of the communication unit **7054a** and the antenna unit **7124** communicate wirelessly with one another, so that information stored in the memory cell **7054h** can be read and information can be written to the memory cell **7054h**. Also, the high-frequency signals that are generated by the communication control module **7123** of the printer main unit **7010a** are induced as a high-frequency magnetic field via the antenna unit **7124**. This high-frequency magnetic field is absorbed via the antenna **7054d** of the communication unit **7054a** and is rectified by the rectifier **7054e**, thus serving as a DC power source for driving the circuits in the non-contact IC chip **7054b**.

The memory cell **7054h** of the communication unit **7054a** stores various types of information, as shown in FIG. 94. The address 00H stores unique ID information for each communication unit, such as the serial number of the communication unit, the address 01H stores the date when the yellow developing container **7054** was manufactured, the address 02H stores information for specifying the destination of the yellow developing container **7054**, the address 03H stores information for specifying the manufacturing line on which the yellow developing container **7054** was manufactured, the address 04H stores information for specifying models with which the yellow developing container **7054** is compatible, the address 05H stores remaining toner amount information as information indicating the amount of toner that is contained in the yellow developing container **7054**, and the address 06H and subsequent regions also store information as appropriate.

The ID information that is stored in the memory cell **7054h** of the communication unit **7054a** can be written at the time that the storage communication unit is manufactured in the factory. By reading this ID information with the printer main unit **7010a**, it is possible to identify the individual communication units **7054a**, **7051a**, **7052a**, and **7053a**.

It should be noted that it is also possible to let the antenna unit **7124** communicate wirelessly with the communication unit **7054a** not only when the developing container holding unit **7050** is standing still but also when the developing container holding unit **7050** is moving. That is, the antenna unit **7124** may be able to communicate wirelessly with the communication unit **7054a** even when the communication unit **7054a** is moving.

==Communication Distance and Communication Region of Communication Units and Antenna Unit==

FIG. 97 is a cross-sectional view, taken from a direction perpendicular to the mounting direction, illustrating the communication distance and the communication region of the communication units and the antenna unit. FIG. 98 is a cross-sectional view, taken from a direction parallel to the mounting

160

direction, illustrating the communication distance and the communication region of the communication units and the antenna unit.

As shown in these drawings, the communication units **7051a**, **7052a**, **7053a**, and **7054a** and the antenna unit **7124** are spaced apart by a communication distance **L**. The communication units **7051a**, **7052a**, **7053a**, and **7054a** are provided, respectively, on the developing containers **7051**, **7052**, **7053**, and **7054**. They are held by the developing container holding unit **7050** and are moved by rotating the developing container holding unit **7050** around its rotation shaft **7050e**. For this reason, the antenna unit **7124**, which is provided on the side of the printer main unit **7010a**, is arranged at a position where it does not come into contact with the portion protruding furthest outward when the developing container holding unit **7050** holding the developing containers **7051**, **7052**, **7053**, and **7054** rotates.

The communication units **7051a**, **7052a**, **7053a**, and **7054a** and the antenna unit **7124** are arranged such that they face each other at the above-mentioned communication position, preferably spaced apart at a communication distance **L** of, for example, 10 mm, at which communication is possible. Moreover, the communication units **7051a**, **7052a**, **7053a**, and **7054a** do not include a power source, so that electric power is supplied to them through carrier waves from the antenna unit **7124**. That is to say, electric power is supplied and signals are transmitted to the communication units **7051a**, **7052a**, **7053a**, and **7054a** through electromagnetic induction occurring between the planar coil-shaped antennas **7054d** and **7124b** with which the communication units **7051a**, **7052a**, **7053a**, and **7054a** and the antenna unit **7124** are respectively provided. For this reason, when the communication units **7051a**, **7052a**, **7053a**, and **7054a** and the antenna unit **7124** communicate, a magnetic flux occurs around the copper foils of the antennas **7051d**, **7052d**, **7053d**, **7054d** and **7124b**. This magnetic flux occurring at the antenna **7124b** of the antenna unit **7124** then has to reach the antennas **7051d**, **7052d**, **7053d**, and **7054d** of the communication units **7051a**, **7052a**, **7053a**, and **7054a**, which are removed by at least the communication distance **L**. That is to say, for the communication units **7051a**, **7052a**, **7053a**, and **7054a** and the antenna unit **7124** to communicate, it is necessary that magnetic flux can be generated in a region of the distance **L** around the copper foils of the antennas **7051d**, **7052d**, **7053d**, **7054d**, and **7124b** (referred to as "communication region **M**" below). Considering the precision of the components of the communication units **7051a**, **7052a**, **7053a**, and **7054a** and the antenna unit **7124** or attachment errors when attaching components to the printer main unit **7010a**, it is preferable that the radius **L**, which defines the communication distance **L** and the communication region **M**, is set to such a distance that favorable communication conditions can be ensured.

In the case of the present embodiment, around the communication units **7051a**, **7052a**, **7053a** and **7054a** and the antenna unit **7124**, a region of the distance **L** from the center of the copper foil constituting the antennas of the communication units and the antenna of the antenna unit becomes the communication region **M**, as shown in FIG. 97 and FIG. 98.

Now, if there are conductive members within this communication region **M**, then the magnetic flux occurring in the antenna **7124b** passes through the conductive members, so that eddy currents flow through these conductive members with the magnetic flux at the axial center and the carrier wave is attenuated significantly. For this reason, the configuration is such that no conductive members are present within the communication region **M**.

161

Now, in the printer 7010 of the present embodiment, a two-component developer made by mixing a non-magnetic toner serving as the developer D and a magnetic carrier is used. That is to say, the magnetic carrier included in the developer is a conductive member, so that carrier waves are also attenuated when developer is present within the communication region M.

More particularly, the developing containers of this embodiment are held by the developing container holding unit 7050, and the positions of the various developing containers are shifted by rotating the developing container holding unit 7050. That is to say, when the developing container holding unit 7050 is rotated once, each developing container is rotated once, too, and is returned to its original state after having been turned upside down. Therefore, it occurs that the developer migrates to the communication unit 7054a. Since the housing 7540 of the developing containers is made of resin, the developer tends to adhere to the inner circumferential surface of the developing containers due to static electricity when the developing containers are rotated. Then, when the developer including the conductive carrier adheres to the inner circumferential surface at the position where the communication unit 7054a is provided, there is the risk that favorable communication is not possible due to the adhering developer, even when the communication unit is positioned on top in the communication position and the developer is positioned below.

The developing container of the present embodiment includes the intrusion prevention section 7546 on the inner side of the position where the communication unit 7054a is provided, in order to partition it from the other regions. This intrusion prevention section 7546 is configured such that no developer intrudes into the region surrounded by the outer circumferential wall of the housing 7540 and the partitioning member 7546a. That is to say, in order to allow favorable communication, the partitioning member 7546a is provided so that it prevents the intrusion of the developer to the side of the communication unit 7054a, so that the outer edge of the partitioning member 7546a on the side of the developer is made larger than the communication region M. That is to say, the region that is partitioned by the partitioning member 7546a includes a region of a distance L from the antenna 7054d of the communication unit 7054a, and is a region that is broader than this region. Therefore, the magnetic flux generated by the antenna 7054d is also generated at least in a region of the distance L on the side of the antenna 7054d that is opposite with respect to the developing container. Thus, it is possible to let the magnetic flux reach the antenna 7124b on the main unit side that is arranged at a spacing of up to the distance L to the antenna 7054d, and to let the magnetic flux generated by the antenna 7124b on the main unit side reach the antenna 7054d. Therefore, it is possible to achieve favorable communication between the antenna 7124b on the main unit side and the antenna 7054d.

With the printer 7010 of the present embodiment, the intrusion prevention section 7546 is provided such that no developer intrudes into the communication region M inside the developing container, so that no conductive carrier obstructing communication is present inside the developing container in the communication region M of the communication units 7051a, 7052a, 7053a, and 7054a and the antenna unit 7124. For this reason, a printer 7010 can be realized, with which favorable communication between the communication units 7051a, 7052a, 7053a, 7054a and the antenna unit 7124 is possible.

In the foregoing embodiment, an example was described, in which the intrusion prevention section is formed by pro-

162

viding a partitioning member 7546 within the housing 7540 of the developing container, but also a configuration is possible in which a concave section for ensuring a region that includes the communication region M and is broader than this communication region M is arranged in the outer circumferential portion of the housing 7540, the intrusion prevention section is formed by providing a lid-shaped partitioning member covering this concave section from the outside, and the communication unit is provided on the outer surface of this lid-shaped partitioning member.

In the foregoing embodiment, an example was described, in which the partitioning member 7546a is provided inside the developing container, a gap is formed between the outer circumferential portion of the housing 7540 and the partitioning member 7546a, and a region that includes the communication region M and is broader than the communication region is partitioned into developer containing sections 7530 and 7531, but it is not necessarily required to form a gap.

FIG. 99 is a diagram showing another working example of an intrusion prevention section. As shown in this diagram, also a configuration of the intrusion prevention section 7546 is possible in which a block made of a resin or urethane or the like, serving as a region holding member 7547 that blocks a region including at least the communication region M, is glued to the inner circumference side of the communication unit, so that the developer will not enter a region broader than the communication region M.

Other Embodiments

An image forming apparatus or the like according to this invention was explained by way of the foregoing embodiment, but the foregoing embodiment of the invention is merely for the purpose of elucidating this invention and is not to be interpreted as limiting this invention. This invention can of course be altered and improved without departing from the gist thereof and equivalents are intended to be embraced therein.

The foregoing embodiment was described for an example of a full-color laser beam printer serving as an image forming apparatus, but the present invention can be applied to image forming apparatuses using the developer including various kinds of magnetic materials, such as monochrome laser beam printers, copiers, facsimile apparatuses, and so on.

Also, in the foregoing embodiment, the photoconductor, which is an image bearing member, was explained as having a photoconductive layer on the outer circumferential surface of a hollow cylindrical conductive member, but there is no limitation to this. For example, it may also be a so-called photoconductive belt, in which a photoconductive layer is provided on the surface of a belt-shaped photoconductive member.

Furthermore, in the foregoing embodiment, as shown in FIG. 85 for example, the mounting and dismounting sections 7050a, 7050b, 7050c, and 7050d are movable, and when the developing containers 7051, 7052, 7053, and 7054 are mounted to the mounting and dismounting sections and are moved to the developing position (first position) through the movement of the mounting and dismounting sections, then the latent image borne on the photoconductor 7020 (image bearing member) provided in the printer main unit 7010a is developed. Moreover, the communication units 7051a, 7052a, 7053a, and 7054a communicate in a noncontacting manner with the printer main unit 7010a when the developing containers 7051, 7052, 7053, and 7054 have been moved to the communication position (second position), which is different from the developing position. However, there is no

limitation to this. For example, it is also possible to let the developing containers not move at all.

And as shown in FIG. 90, the communication units **7051a**, **7052a**, **7053a**, and **7054a** are attached at positions of the circularly arc-shaped surface **7543a** that are furthest removed from the developing rollers **7510**. However, there is no limitation to this. For example, it is also possible that the communication units are attached at positions of the circularly arc-shaped surface **7543a** that are close to the developing rollers **7510**.

However, if the communication units **7051a**, **7052a**, **7053a**, and **7054a** are attached at the positions of the circularly arc-shaped surface **7543a** that are furthest removed from the developing rollers **7510**, then it can be prevented that the toner T borne on the developing rollers **7510** is scattered and adheres to the communication units, so that the communication units can communicate more properly with the printer main unit **7010a**. For this reason, the above-described embodiment is more preferable.

==Configuration of Image Forming System Etc.==

Next, an embodiment of an image forming system serving as an example of an embodiment of the present invention is described with reference to the drawings.

FIG. 100 is an explanatory diagram showing the external configuration of an image forming system. An image forming system **7700** is provided with a computer **7702**, a display device **7704**, a printer **7010**, input devices **7708**, and reading devices **7710**.

In this embodiment, the computer **7702** is contained within a mini-tower type housing, but there is no limitation to this. A CRT (cathode ray tube), plasma display, or liquid crystal display device, for example, is generally used as the display device **7704**, but there is no limitation to this. As the printer **7010**, the printer described above is used. In this embodiment, the input devices **7708** are a keyboard **7708A** and a mouse **7708B**, but there is no limitation to these. In this embodiment, a flexible disk drive device **7710A** and a CD-ROM drive device **7710B** are used as the reading devices **7710**, but the reading devices **7710** are not limited to these, and may also include an MO (magneto-optical) disk drive device or a DVD (digital versatile disk), for example.

FIG. 101 is a block diagram showing the configuration of the image forming system shown in FIG. 100. An internal memory **7802** such as a RAM is provided within the casing containing the computer **7702**, and furthermore an external memory such as a hard disk drive unit **7804** is provided.

In the above explanations, an example was given in which the image forming system is constituted by connecting the printer **7010** to the computer **7702**, the display device **7704**, the input devices **7708**, and the reading devices **7710**, but there is no limitation to this. For example, the image forming system may also be made of the computer **7702** and the printer **7010**, and the image forming system does not have to be provided with any one of the display device **7704**, the input devices **7708**, and the reading devices **7710**.

It is also possible that the printer **77010** has some of the functions or mechanisms of each of the computer **7702**, the display device **7704**, the input devices **7708** and the reading devices **7710**, for example. For example, the printer **77010** may be configured so as to have an image processing section for carrying out image processing, a display section for carrying out various types of displays, and a recording media mounting and dismounting section into and from which recording media storing image data captured by a digital camera or the like are inserted and taken out.

As an overall system, the image forming system that is thus achieved is superior to conventional systems.

Overview of Image Forming Apparatus of Ninth Embodiment

5

Referring to FIGS. 102 to 107, an overview of a laser beam printer (hereinafter, also referred to as "printer") **8010** serving as an example of an image forming apparatus is described. 10 FIG. 102 is a diagram illustrating the configuration of a printer **8010** with respect to which developing containers **8051**, **8052**, **8053** and **8054** can be mounted and dismounted. FIG. 103 is a diagram showing the main structural components constituting the printer **8010**. FIG. 104 is a block diagram showing the control unit **8100** of the printer **8010**. FIG. 15 105 is a perspective view of a developing container holding unit **8050**. FIG. 106 is a diagram showing the developing container holding unit **8050** in a state in which a yellow developing container **8054** is mounted to a mounting and dismounting section **8050d**. FIG. 107 is a diagram showing the 20 positions of the mounted developing container and the developing container holding unit. It should be noted that FIG. 103 is a diagram of a cross section taken perpendicular to the mounting direction of the developing container, for example, in FIG. 102. Also, the vertical direction is indicated by arrows in FIG. 102 and FIG. 103, and for example, a paper supply tray **8092** is disposed at a lower part of the printer **8010** and a fixing unit **8090** is disposed at an upper part of the printer **8010**.

30 <Mounting and Dismounting Configuration>

Developing containers **8051**, **8052**, **8053** and **8054**, which are configured as cartridges and are examples of developing devices, and a photoconductor unit **8075**, which is an example of an image bearing member unit, can be mounted and dismounted with respect to the printer **8010**, which is an example of an image forming apparatus. 35

The printer **8010** has a first opening and closing cover **8010b** that can be opened and closed, a second opening and closing cover **8010c** that can be opened and closed and that is provided further inward than the first opening and closing cover **8010b**, a photoconductor unit mounting and dismounting opening **8010d** through which the photoconductor unit **8075** can be mounted and dismounted, and a developing container mounting and dismounting opening **8010e** serving as an opening through which the developing containers **8051**, **8052**, **8053**, and **8054** can be mounted and dismounted. 40

45 Here, by opening the first opening and closing cover **8010b**, the user can mount and dismount the photoconductor unit **8075**, which is configured as a cartridge, with respect to the printer **8010** through the photoconductor unit mounting and dismounting opening **8010d**. Further, by opening the second opening and closing cover **8010c**, the user can mount and dismount the developing containers **8051**, **8052**, **8053**, and **8054** configured as cartridges with respect to the printer **8010** through the developing container mounting and dismounting opening **8010e**. 50

55 <Configuration of the Printer 8010>

The configuration of the printer **8010** in a state in which the 60 developing containers **8051**, **8052**, **8053**, and **8054** and the photoconductor unit **75** are mounted to the printer **8010** is described next.

As shown in FIG. 103, the printer **8010** according to this embodiment includes a charging unit **8030**, an exposing unit **8040**, a developing container holding unit **8050**, a first image transfer unit **8060**, an intermediate image transfer member **8070**, and a cleaning blade **8076**. These units are arranged 65

165

along the rotation direction of a photoconductor **8020**, which is an example of an image bearing member bearing a latent image. The printer **8010** further includes a second image transfer unit **8080**, a fixing unit **8090**, a display unit **8095** constituted by a liquid-crystal panel and serving as a means for giving notifications to the user, a control unit **8100** for controlling these units and managing the operations of the printer, and a power source unit **8098** covered by a power source shielding member **8098a**.

The photoconductor **8020**, the charging unit **8030**, the exposing unit **8040**, the developing container holding unit **8050**, the primary image transfer unit **8060**, the intermediate image transfer member **8070**, the cleaning blade **8076**, the secondary image transfer unit **8080**, the fixing unit **8090**, the control unit **8100**, and the power source unit **8098** are disposed in the mounting direction at intervals from the upstream side and the downstream side in a metal frame **8010f** serving as a casing of the printer **8010**. Moreover, between these elements and the frame **8010f**, a metal stay **8010g** is disposed on both ends in the direction intersecting with the mounting direction.

Furthermore, the printer **8010** is provided with a mounting shielding member for shielding electromagnetic waves intruding from the outside, and the printer **8010** is covered substantially entirely by this shielding member. That is to say, the frame **8010f** and the stay **8010g** that make up the casing also function as shielding members.

Furthermore, around the developing container holding unit **8050**, an exhaust duct **8066** is provided that serves as a passageway for air to be exhausted out of the apparatus by sucking out air inside the printer **8010**, that is, the image forming apparatus. The exhaust duct **8066** is explained later.

The photoconductor **8020** has a hollow cylindrical conductive base and a photoconductive layer formed on the outer circumferential surface of the conductive base, and is rotatable around its center axis. In this embodiment, the photoconductor **8020** rotates clockwise, as indicated by the arrow in FIG. 103. The charging unit **8030** is a device for charging the photoconductor **8020**. In the printer **8010** of the present embodiment, the photoconductor **8020**, the cleaning blade **8076**, and the charging unit **8030** are configured as one photoconductor unit **8075** provided with a waster toner container.

The exposing unit **8040** is a device for forming a latent image on the photoconductor **8020**, which has been charged by irradiating a laser beam on the photoconductor **8020**. The exposing unit **8040** includes, for example, a semiconductor laser, a polygon mirror, and an F-0 lens, and irradiates a modulated laser beam onto the charged photoconductor **8020** in accordance with image signals that have been input from a host computer not shown in the drawings, such as a personal computer or a word processor.

The developing container holding unit **8050** is a device for developing the latent image formed on the photoconductor **8020** using toner **T**, which is an example of a developer contained in developing containers **8051**, **8052**, **8053**, and **8054**, that is, black (K) toner contained in a black developing container **8051**, magenta (M) toner contained in a magenta developing container **8052**, cyan (C) toner contained in a cyan developing container **8053**, and yellow (Y) toner contained in a yellow developing container **8054**.

This developing container holding unit **8050** includes a rotation shaft **8050e** and four mounting and dismounting sections **8050a**, **8050b**, **8050c**, and **8050d** with respect to which the developing containers **8051**, **8052**, **8053**, and **8054** can be mounted and dismounted and which are disposed at intervals of 90° in circumferential direction around the rotation shaft **8050e**. Each of the mounting and dismounting

166

sections **8050a**, **8050b**, **8050c**, and **8050d** is provided in the same space, partitioned by two neighboring wall sections **8050f** of the four wall sections **8050f** formed at intervals of 90° in four radial directions from the rotation shaft **8050e** provided in the middle of the developing container holding unit **8050**. That is to say, the mounting and dismounting section **8050a** with respect to which the black developing container **8051** can be mounted and dismounted, the mounting and dismounting section **8050b** with respect to which the magenta developing container **8052** can be mounted and dismounted, the mounting and dismounting section **8050c** with respect to which the cyan developing container **8053** can be mounted and dismounted, and the mounting and dismounting section **8050d** with respect to which the yellow developing container **8054** can be mounted and dismounted are disposed at intervals of 90° in circumferential direction around the rotation shaft **8050e** in the developing container holding unit **8050**.

It is possible to move the positions of the four developing containers **8051**, **8052**, **8053**, and **8054** that are held by moving the mounting and dismounting sections **8050a**, **8050b**, **8050c**, and **8050d** through the rotation of the developing container holding unit **8050** around the rotation shaft **8050e**. That is to say, the four developing containers **8051**, **8052**, **8053**, and **8054** can be rotated around the rotation shaft **8050e** while maintaining their relative positions. Then, when the developing containers **8051**, **8052**, **8053**, and **8054** are mounted to the mounting and dismounting sections **8050a**, **8050b**, **8050c**, and **8050d** and are moved to the developing position through the movement of the mounting and dismounting sections **8050a**, **8050b**, **8050c**, and **8050d**, the latent image borne by the photoconductor **8020** is developed with the toner contained in the respective developing containers **8051**, **8052**, **8053**, and **8054**. It should be noted that details of the developing containers are discussed later.

As shown in FIG. 105, the mounting and dismounting sections **8050a**, **8050b**, **8050c**, and **8050d** are each provided with coupling holes **8059** into which coupling protrusions provided on a coupling member **8590** (see FIG. 108) of each developing container can be fitted, a guiding section **8056** for guiding the developing container by engaging with a guided section **8549** provided on the developing container that is inserted from the developing container mounting and dismounting opening **8010e**, and springs **8576** for biasing the developing containers toward the outer circumferential direction of the developing container holding unit **8050**. For example, coupling pins **8595a** and **8595b** (see FIG. 112), which are examples of coupling protrusions provided on the coupling member **8590** of the yellow developing container **8054**, as shown in FIG. 106, are fitted into the coupling holes **8059** provided in the mounting and dismounting section **8050d**.

And as shown in FIG. 107, the guiding sections **8056** are provided on each of the two wall sections **8050f** constituting the mounting and dismounting section. The guiding sections **8056** have perpendicular surfaces formed on the respective wall sections **8050f** and are arranged extending along the longitudinal direction of the yellow developing container **8054**, protruding on the side of the same space partitioned by two adjacent wall sections **8050f**. That is to say, the guiding sections **8056**, which are provided on adjacent wall sections **8050f** facing toward the same space, are formed such that their surfaces both face toward the rotation shaft **8050e** side and their surfaces define an angle of substantially 90°. The yellow developing container **8054** is mounted by arranging the guided sections **8549** of the yellow developing container **8054** such that they are on the side of the rotation shaft **8050e**.

with respect to the two perpendicular surfaces of the guiding sections **8056**, and inserting the guided sections **8549** along the guiding sections **8056**.

The springs **8576** provided on the mounting and dismounting section **8050d** bias the yellow developing container **8054** toward the outer circumferential direction of the developing container holding unit **8050**. Thus, when the yellow developing container **8054** is inserted from the developing container mounting and dismounting opening **8010e** with the guided sections **8549** being arranged on the side of the rotation shaft **8050e** with respect to the perpendicular surfaces of the guiding sections **8056**, the yellow developing container **8054** is biased by the springs **8576** toward the outer circumferential direction. Moreover, as shown in FIG. 105, the mounting and dismounting sections **8050a**, **8050b**, **8050c**, and **8050d** are each provided with a positioning hole **8058** into which a positioning pin **8588** (see FIG. 108) or the respective developing container can be fitted. That is to say, by fitting the positioning pin **8588** provided on the yellow developing container **8054** into the positioning hole **8058** provided in the mounting and dismounting section **8050d**, the yellow developing container **8054** is mounted by positioning it in a predetermined position.

The primary image transfer unit **8060** is a device for transferring a single color toner image formed on the photoconductor **8020** to the intermediate image transfer member **8070**. When the four toner colors are successively transferred over one another, a full color toner image is formed on the intermediate image transfer member **8070**. This intermediate image transfer member **8070** is an endless belt that is rotatively driven at substantially the same circumferential velocity as the photoconductor **8020**.

The secondary image transfer unit **8080** is a device for transferring a single color toner image or a full color toner image formed on the intermediate image transfer member **8070** to a recording medium such as paper, film, or cloth. The fixing unit **8090** is a device for fusing the single color toner image or the full color toner image that has been transferred to the recording medium on the recording medium, such as paper, making it a permanent image.

The cleaning blade **8076** is made of rubber and is in contact with the surface of the photoconductor **8020**. The cleaning blade **8076** scrapes off and removes toner remaining on the photoconductor **8020**, after the toner image has been transferred to the intermediate image transfer body **8070** by the primary image transfer unit **8060**.

The photoconductor unit **8075** is provided between the primary image transfer unit **8060** and the exposing unit **8040**, and includes the photoconductor **8020**, the charging unit **8030**, the cleaning blade **8076**, and a waste toner container not shown in the drawings containing toner that has been wiped away by the cleaning blade **8076**.

The control unit **8100** is made of a main controller **8101** and a unit controller **8102**, as shown in FIG. 104. An image signal is input into the main controller **8101**, and in accordance with a command based on this image signal, the unit controller **8102** controls the various units, for example, to form the image.

<Operation of the Printer **8010**>

The operation of the printer **8010** configured as above is described below, referring to other structural components thereof as well.

First, when an image signal from a host computer not shown in the drawings is input into the main controller **8101** of the printer **8010** via an interface (I/F) **8112**, the photoconductor **8020**, developing rollers **8510** provided in the devel-

oping containers **8051**, **8052**, **8053**, and **8054**, and the intermediate image transfer member **8070** are rotated under the control of the unit controller **8102** based on a command from the main controller **8101**. While rotating, the photoconductor **8020** is successively charged by the charging unit **8030** at a charging position.

The region of the photoconductor **8020** that has been charged is brought to an exposure position through rotation of the photoconductor **8020**, and a latent image corresponding to image information of a first color, for example yellow Y, is formed at that region by the exposing unit **8040**. Moreover, the developing container holding unit **8050** positions the yellow developing container **8054** containing the yellow (Y) toner at the developing position opposite the photoconductor **8020**.

The latent image formed on the photoconductor **8020** is brought to a developing position through the rotation of the photoconductor **8020**, and is developed with yellow toner by the yellow developing container **8054**. Thus, a yellow toner image is formed on the photoconductor **8020**.

The yellow toner image that is formed on the photoconductor **8020** is brought to the primary image transfer position through rotation of the photoconductor **8020** and is transferred to the intermediate image transfer member **8060** by the primary image transfer unit **8070**. At this time, a primary image transfer voltage of a polarity that is opposite the toner charge polarity is applied to the primary image transfer unit **8060**. It should be noted that throughout this operation, the secondary image transfer unit **8080** is removed from the intermediate image transfer member **8070**.

The above process is repeated for a second color, a third color, and a fourth color, thereby transferring toner images of four colors corresponding to various image signals layered over one another onto the intermediate image transfer unit **8070**. Thus, a full color toner image is formed on the intermediate image transfer member **8070**.

The full color toner image that is formed on the intermediate image transfer member **8070** is brought to the secondary image transfer position through the rotation of the intermediate image transfer member **8070** and is transferred to a recording medium such as paper by the secondary image transfer unit **8080**. It should be noted that the recording medium is carried from the paper supply tray **8092** to the secondary image transfer unit **8080** via a paper supply roller **8094** and registration rollers **8096**. Also, when performing the image transfer operation, the secondary image transfer unit **8080** is pressed against the intermediate image transfer member **8070** while applying a secondary image transfer voltage to it.

The fixing unit **8090** heats and applies pressure to the full color toner image that has been transferred to the recording medium, thus fusing it to the recording medium. On the other hand, after the photoconductor **8020** has passed the primary image transfer position, the toner adhering to its surface is scraped off by the cleaning blade **8076**, and it is provided with a charge for forming the next latent image. The toner that is scraped off is collected in the waste toner container.

==Overview of the Control Unit==

The configuration of the control unit **8100** is described next, with reference to FIG. 104. The control unit **8100** includes the main controller **8101** and the unit controller **8102**.

The main controller **8101** includes a CPU **8111**, an interface **8112** for connection to a computer not shown in the drawings, an image memory **8113** for storing image signals input from the computer, and a main controller-side memory

8114 made of an EEPROM **8114a** that can be rewritten electrically, a RAM **8114b**, an a program ROM or the like in which a program for the various kinds of control is stored.

The CPU **8111** of the main controller **8101** controls the reading in and the reading out of image data that has been input via the interface into the image memory **8113**, and performs the control of the overall apparatus in synchronization with the CPU **8120** of the unit controller **8102** based on the control signals input from the computer.

The unit controller **8102** includes the CPU **8120**, a unit controller-side memory **8116** including an EEPROM **8116a** that can be rewritten electrically, a RAM and a program ROM or the like in which a program for the various kinds of control is stored, as well as drive control circuits or the like for performing drive control of the various units of the entire device (the charging unit **8030**, the exposing unit **8040**, the developing container holding unit **8050**, the primary image transfer unit **8060**, the photoconductor unit **8075**, the secondary image transfer unit **8080**, the fixing unit **8090** and the display unit **8095**).

The CPU **8120** of the unit controller **8102** is electrically connected to the various drive control circuits and controls the various drive control circuits in accordance with control signals from the CPU **8111** of the main controller **8101**. That is to say, while the state of the units is detected by receiving signals from sensors or the like provided in each of the units, the units are controlled in accordance with signals input from the main controller **8101**.

Also, the CPU **8120** provided in the unit controller **8102** is connected to a non-volatile storage element (hereinafter, also referred to as "main unit-side memory") **8122** such as a serial EEPROM via the serial interface (I/F) **8121**. This main unit-side memory **8122** stores data that is necessary for the control of the apparatus.

Furthermore, the CPU **8120** is capable of wirelessly communicating with communication units **8051a**, **8052a**, **8053a**, and **8054a**, which are respectively provided in the developing containers **8051**, **8052**, **8053**, and **8054**, via the serial interface **8121**, a communication control module **8123** serving as an antenna driving circuit and an antenna unit **8124** serving as an apparatus-side antenna. Through the communication of the antenna unit **8124** and the communication units **8051a**, **8052a**, **8053a**, and **8054a**, the control unit **8100** can write information into the communication units **8051a**, **8052a**, **8053a**, and **8054a** provided in the developing containers **8051**, **8052**, **8053**, and **8054**, as well as read in information from the communication units **8051a**, **8052a**, **8053a**, and **8054a** provided in the developing containers **8051**, **8052**, **8053**, and **8054**. The communication units **8051a**, **8052a**, **8053a**, **8054a** and the antenna unit **124** are explained further below.

====Overview of the Developing Containers====

The configuration and operation of the developing containers **8051**, **8052**, **8053**, and **8054** is explained next, using FIG. 108 to FIG. 112. FIG. 108 is a perspective view of the yellow developing container **8054**. FIG. 109 is a cross-sectional view showing the main structural components of the yellow developing container **8054**. FIG. 110 is a perspective view of a developing roller **8510** provided with rolls **8574**. FIG. 111 is a front view of the coupling member **8590**. FIG. 112 is a perspective view showing the rear side of the coupling member **8590**. It should be noted that the cross-sectional view in FIG. 109 shows a cross section of the yellow developing container **8054** taken along a plane that is perpendicular to the longitudinal direction shown in FIG. 108. Moreover, in FIG. 109, like in FIG. 102, the vertical direction is indicated by

arrows, and for example, the center axis of the developing roller **8510** is lower than the center axis of the photoconductor **8020**. Also, in FIG. 109, the yellow developing container **8054** is shown positioned at a developing position that is in opposition to the photoconductor **8020**.

The black developing container **8051** containing black (K) toner, the magenta developing container **8052** containing magenta (M) toner, the cyan developing container **8053** containing cyan (C) toner, and the yellow developing container **8054** containing yellow (Y) toner can be mounted to the developing container holding unit **8050**, but since the configuration and the operation of each of the developing containers is the same, explanations are given only for the yellow developing container **8054** in the following.

15 <Internal Configuration of the Yellow Developing Container **8054**>

First, the configuration of the yellow developing container **8054** is described. The yellow developing container **8054** includes the developing roller **8510**, which is an example of a developer carrying member, a toner containing section **8530**, a housing **8540** containing toner T, a toner supply roller **8550**, a regulating blade **8560**, a sealing member **8520**, a positioning shaft (also referred to as "positioning pin" in this embodiment) **8588** serving as an example of a positioning member and a coupling member **8590**.

20 The developing roller **8510** bears toner T and carries it to the developing position opposite the photoconductor **8020**, and develops the latent image borne on the photoconductor **8020** with the toner T carried to the developing position. This developing roller **8510**, which is made of metal, is fabricated from an aluminum alloy, such as 5056 aluminum alloy or 6063 aluminum alloy, or an iron alloy such as STKM, and may be nickel-plated or chromium-plated if necessary. As shown in FIG. 110, the developing roller **8510** includes a large-diameter section **8510a** and shaft sections **8510b**.

25 Moreover, as shown in FIG. 108, the developing roller **8510** is supported by the housing **8540** at its two end portions in the longitudinal direction, that is, at the shaft sections **8510b**, and can be rotated around its center axis. As shown in FIG. 109, the developing roller **8510** rotates in a direction (the counterclockwise direction in FIG. 109) that is opposite to the rotation direction of the photoconductor **8020** (the clockwise direction in FIG. 109). Its center axis is lower than the center axis of the photoconductor **8020**.

30 Also, as shown in FIG. 109, in a state where the yellow developing container **8054** is in opposition to the photoconductor **8020**, there is a gap between the developing roller **8510** and the photoconductor **8020**. That is to say, the yellow developing container **8054** develops the latent image formed on the photoconductor **8020** in a noncontacting manner. It should be noted that during the development of the latent image formed on the photoconductor **8020**, an alternating electric field is formed between the developing roller **8510** and the photoconductor **8020**.

35 Furthermore, as shown in FIG. 110, rolls **8574**, which are an example of distance holding members, are formed on both end portions in the longitudinal direction of the developing roller **8510**. When the developing containers **8051**, **8052**, **8053**, and **8054** are positioned in the developing position, these rolls **8574** have the function of coming into contact with the photoconductor **8020** and thereby holding a constant distance between the photoconductor **8020** and the developing roller **8510**. The rolls **8574** are slid rotatably onto the shaft sections **8510b**. The outer diameter of the rolls **8574** is larger than the outer diameter of the large-diameter section **8510a**. Therefore, it is possible to hold a constant distance between

the developing roller 8510 and the photoconductor 8020 by rotating the rolls 8574 while they contact the photoconductor 8020.

The sealing member 8520 prevents the toner T in the yellow developing container 8054 from leaking to the outside, and also collects toner T on the developing roller 8510, after it has passed the developing position, into the developing container without scraping it off. This sealing member 8520 is a seal made of polyethylene film or the like. The sealing member 8520 is supported by a seal support metal plate 8522, and is attached to the housing 8540 via the seal support metal plate 8522. Furthermore, a seal biasing member 8524 made of Moltopren or the like is provided on the side of the sealing member 8520 that is opposite to its developing roller 8510 side, and due to the elasticity of the seal biasing member 8524, the sealing member 8520 is pressed against the developing roller 8510. It should be noted that the contact position where the sealing member 8520 contacts the developing roller 8510 is above the center axis of the developing roller 8510.

The housing 8540 is fabricated by welding together a plurality of integrally molded housing sections, namely an upper housing section 8542 and a lower housing section 8544. A partitioning wall 8545 for partitioning the inside of the housing, which protrudes from the inner wall to the inside (vertically in FIG. 109), partitions the housing 8540 into two toner containing sections 8530, namely a first toner containing section 8530a and a second toner containing section 8530b. It should be noted that the housing 8540 has a housing opening 8572 at its bottom portion, and the developing roller 8510 is arranged such that a portion of it is exposed in this housing opening 8572. Moreover, a communication unit 8054a is attached to the housing 8540. The configuration of this communication unit 8054a and the position at which it is attached to the housing 8540 are explained later.

A second side wall 8547, which is arranged on the frontward side of the printer 8010 in the longitudinal direction of the housing 8540, is provided with attachment protrusions 8581a and 8581b (see FIG. 111). The attachment protrusion 8581a can be fitted into an attachment hole 8593a of the later-explained coupling member 8590, and the attachment protrusion 8581b can be fitted into an attachment hole 8593b of the coupling member 8590. The attachment protrusions 8581a and 8581b have a circular cross section.

Moreover, the toner containing section 8530 may be provided with a stirring member for stirring the toner T, but in the present embodiment, the developing containers (the black developing container 8051, the magenta developing container 8052, the cyan developing container 8053 and the yellow developing container 8054) rotate with the rotation of the developing container holding unit 8050, and this stirs the toner T inside the developing containers, so that the toner containing section 8530 is not provided with a stirring member.

The toner supply roller 8550 is provided in the above-mentioned first toner containing section 8530a and not only supplies toner T that is contained in this first toner containing section 8530a to the developing roller 8510, but also scrapes off, from the developing roller 8510, toner T that has remained on the developing roller 8510 after developing. The toner supply roller 8550 is made of polyurethane foam, for example, and is in contact with the developing roller 8510 in a state of elastic deformation. The toner supply roller 8550 is disposed at the bottom portion of the toner containing section 8530, and the toner T contained in the containing section 8530 is supplied to the developing roller 8510 by this toner supply roller 8550 at the bottom portion of the toner contain-

ing section 8530. The toner supply roller 8550 rotates in a direction (the clockwise direction in FIG. 109) that is opposite the rotation direction of the developing roller 8510 (the counterclockwise direction in FIG. 109). Its center axis is lower than the rotation center axis of the developing roller 8510.

The regulating blade 8560 applies a charge to the toner T borne on the developing roller 8510 and regulates the layer thickness of the toner T borne on the developing roller 8510. The regulating blade 8560 has a rubber part 8560a and a rubber supporting part 8560b. The rubber part 8560a is made of silicone rubber or urethane rubber, for example, and the rubber supporting part 8560b is a thin plate of phosphor bronze or stainless steel, for example, and has elasticity. The rubber part 8560a is supported by the rubber supporting part 8560b, and the rubber supporting part 8560b is attached to the housing 8540 via a blade support metal plate 8562, with one end portion of the rubber supporting part 8560b being supported by the blade support metal plate 8562. Also, a blade backing member 8570 made of Moltopren or the like is provided on the side of the regulating blade 8560 that is opposite the side of the developing roller 8510.

Here, the rubber part 8560a is pressed against the developing roller 8510 by the elastic force due to the bending of the rubber supporting part 8560b. The blade backing member 8570 prevents the toner T from entering in between the rubber supporting part 8560b and the housing 8540, and stabilizes the elasticity due to the bending of the rubber supporting part 8560b while pressing the rubber part 8560a against the developing roller 8510 by urging the rubber part 8560a toward the developing roller 8510 from directly behind the rubber part 8560a. Consequently, the blade backing member 8570 makes the contact of the rubber part 8560a with the developing roller 8510 more uniform.

The end of the regulating blade 8560 on the side opposite the side supported by the blade support metal plate 8562, that is, its front end, is not in contact with the developing roller 8510, and a portion thereof removed from this front end by a predetermined distance is in contact with the developing roller 8510 over a certain width. That is to say, the regulating blade 8560 does not come into contact with the developing roller 8510 at its edge but rather at a mid section thereof. Also, the regulating blade 8560 is disposed such that its front end is facing upstream with respect to the direction in which the developing roller 8510 rotates, and is in so-called counter contact. It should be noted that the contact position where the regulating blade 8560 contacts the developing roller 8510 is below the center axis of the developing roller 8510 and is below the center axis of the toner supply roller 8550.

<Configuration of the Positioning Member>

The following is a description of the configuration of the positioning pin 8588. As shown in FIG. 108, the positioning pin 8588 is provided on a one end side in the longitudinal direction of the yellow developing container main unit, which is an example of a developing device main unit, that is, on the downstream side with respect to the direction in which the developing container is mounted.

This positioning pin 8588 has the function of positioning the yellow developing container main unit with respect to the mounting and dismounting section 8050d by engaging the mounting and dismounting section 8050d, or more specifically by fitting into the positioning hole 8058 provided on the mounting and dismounting section 8050d, as shown in FIG. 106, when the yellow developing container 8054 is mounted to the mounting and dismounting section 8050d.

Moreover, the positioning pin **8588**, which is made of metal, is arranged such that its axial direction extends in the longitudinal direction of the developing container main unit. One end of the positioning pin **8588** is fixed to a first side wall **8546** of the housing **8540**, on the downstream side with respect to the mounting direction. The front end of the positioning pin **8588** is tapered, so that it can be easily fitted into the positioning hole **8058** of the mounting and dismounting section **8050d**.

<Configuration of the Coupling Member>

The configuration of the coupling member **8590** is described next. As shown in FIG. 108, the coupling member **8590** is attached to the upstream side, with respect to the mounting direction, of the yellow developing container main unit.

As shown in FIG. 112, the coupling member **8590** is provided with coupling pins **8595a** and **8595b**, which are an example of coupling protrusions that can be fitted into the coupling holes **8059** of the mounting and dismounting section **8050d**. When the yellow developing container **8054** is mounted to the mounting and dismounting section **8050d**, the coupling pins **8595a** and **8595b** are fitted into the coupling holes **8059** provided in the mounting and dismounting section **8050d**. Thus, when the yellow developing container **8054** is mounted to the mounting and dismounting section **8050d**, the coupling member **8590** is coupled to the mounting and dismounting section **8050d**. It should be noted that when the coupling member **8590** is coupled to the mounting and dismounting section **8050d**, the movement of the coupling member **8590** with respect to the mounting and dismounting section **8050d** is restricted.

Furthermore, as shown in FIG. 111, the coupling member **8590** includes an attachment hole **8593a** into which the attachment protrusion **8581a** provided on the second side wall **8547** on the other end side in the longitudinal direction of the housing **8540**, that is, the upstream side with respect to the mounting direction of the developing container, can be fitted, and an attachment hole **8593b** into which the attachment protrusion **8581b** can be fitted. When the attachment protrusion **8581a** is fitted into the attachment hole **8593a** and the attachment protrusion **8581b** is fitted into the attachment hole **8593b**, the coupling member **8590** is attached to the side wall on the upstream side in the mounting direction of the housing **8540**, that is, of the developing container, by stopping screws **8598** via the coupling member **8590** with respect to screw holes provided in the attachment protrusion **8581a** and the attachment protrusion **8581b**, as shown in FIG. 106.

Moreover, as shown in FIG. 111, the attachment hole **8593a** and the attachment hole **8593b** have a substantially elliptical cross section. The attachment hole **8593a** and the attachment hole **8593b** are provided such that the directions of the major axes of the substantially elliptical cross sections are the same direction. Moreover, as noted above, the cross section of the attachment protrusion **8581a** is circular. Consequently, the attachment hole **8593a** allows movement of the attachment protrusion **8581a**, which is fitted into the attachment hole **8593a**, within the attachment hole **8593a**. Similarly, the attachment hole **8593b** allows movement of the attachment protrusion **8581b**, which is fitted into the attachment hole **8593b**, within the attachment hole **8593b**.

That is to say, the attachment hole **8593a** allows movement of the attachment protrusion **8581a** within the attachment hole **8593a** in the direction of the major axis of its substantially elliptical cross section, and the attachment hole **8593b** allows movement of the attachment protrusion **8581b** within the attachment hole **8593b** in the direction of the major axis of

its elliptical cross section. It should be noted that the movement of the attachment protrusion **8581a** within the attachment hole **8593a** and the movement of the attachment protrusion **8581b** within the attachment hole **8593b** occur at the same timing. Thus, the coupling member **8590** is attached in such a manner that its relative position to the developing container main unit can be changed.

<Operation of the Yellow Developing Container **8054**>

Next, the operation of the yellow developing container **8054** is described. In the yellow developing container **8054** configured in this manner, the toner T that is contained in the toner containing section **8530** is supplied to the developing roller **8510** by rotating the toner supply roller **8550**.

As the developing roller **8510** rotates, the toner T that is supplied to the developing roller **8510** is brought to the contact position of the regulating blade **8560**, and when it passes that contact position, the layer thickness of the toner T is regulated, and a charge is applied to it. The toner T on the developing roller **8510**, whose layer thickness has been regulated and which has been charged, is brought to the developing position in opposition to the photoconductor **8020** by further rotation of the developing roller **8510**, and is supplied for the development of the latent image formed on the photoconductor **8020** in an alternating electric field at the developing position.

The toner T on the developing roller **8510** that has passed the developing position due to further rotation of the developing roller **8510** passes the upper sealing member **8520** and is collected in the developing device without being scraped off by the upper sealing member **8520**. Moreover, the toner T that still remains on the developing roller **8510** is stripped off by the toner supply roller **8550**.

====The Developing Position, Communication Position and Mounting and Dismounting Position of the Developing Containers====

As mentioned above, the developing containers **8051**, **8052**, **8053**, and **8054** are moved together with the movement of the mounting and dismounting sections **8050a**, **8050b**, **8050c**, and **8050d**. At that time, the mounting and dismounting sections are moved such that the developing containers are positioned in predetermined positions. Such predetermined positions are the developing position serving as a first position, the communication position serving as a second position, and the mounting and dismounting position. Since the developing position, the communication position and the mounting and dismounting position of each of the developing containers are the same, the developing position, the communication position, and the mounting and dismounting position of the yellow developing container **8054** are explained in the following with reference to FIGS. 113A to 113D. FIG. 113A is a diagram showing the developing container holding unit **8050** in a state where the yellow developing container **8054** is positioned at the developing position. FIG. 113B is a diagram showing the developing container holding unit **8050** in a state where the yellow developing container **8054** is positioned at the communication position. FIG. 113C is a diagram showing the developing container holding unit **8050** in a state where the yellow developing container **8054** is positioned at the mounting and dismounting position. FIG. 113D is a diagram showing a state where the developing container holding unit **8050** is positioned in its home position.

In the state shown in FIG. 113A, the yellow developing container **8054** is positioned at the developing position in which the developing roller **8510** is in opposition to the photoconductor **8020**. In this state, the developing roller **8510** is able to develop the latent image borne on the photoconductor

8020. In the state in which the yellow developing container **8054** is positioned in the developing position, as noted above, the springs **8576** provided in the mounting and dismounting section **8050d** bias the yellow developing container main unit towards the outer circumferential side. Due to this spring force of the springs **8576**, the rolls **8574** come into contact with the photoconductor **8020**. It should be noted that when the photoconductor **8020** is installed in a slanted manner with respect to the printer **8010**, then the yellow developing container main unit moves with respect to the coupling member **8590** when the yellow developing container **8054** is positioned in the developing position, that is, the attachment protrusion **8581a** of the yellow developing container main unit moves in the major axis direction within the attachment hole **8593a** of the coupling member and the attachment protrusion **8581b** of the yellow developing container main unit moves in the major axis direction within the attachment hole **8593b** of the coupling member **8590**, so that the rolls **8574** with which the yellow developing container main unit is provided contact suitably with the photoconductor **8020**. During this, the relative position of the developing container main unit and the coupling member **8590** is changed in accordance with the spring force of the springs **8576**. It should be noted that in a state in which the yellow developing container **8054** is positioned in the developing position, the magenta developing container **8052** is positioned in the communication position.

Furthermore, when the developing container holding unit **8050** is rotated for a predetermined angle in Z-direction in FIG. 113A from the state shown in FIG. 113A around its rotation shaft **8050e**, then the state shown in FIG. 113B is achieved. In the state shown in FIG. 113B, the yellow developing container **8054** is positioned in the communication position. In this state, the communication unit **8054a** provided on the yellow developing container **8054** opposes the antenna unit **8124** in a noncontacting manner. This communication unit **8054a** can then communicate with the antenna unit **8124**. Furthermore, when the yellow developing container **8054** is positioned in the communication position, the rolls **8574** of the yellow developing container **8054** do not come into contact with members on the side of the printer **8010**. It should be noted that when the yellow developing container **8054** is positioned in the communication position, the black developing container **8051** is positioned in the developing position. Therefore, the communication between the antenna unit **8124** and the communication element **8054a** can take place while the black developing container **8051** develops the latent image borne on the photoconductor **8020**.

Furthermore, when the developing container holding unit **8050** is rotated around its rotation shaft **8050e** for a predetermined angle in Z-direction in FIG. 113B from the state shown in FIG. 113B, then the state shown in FIG. 113C is achieved. In the state shown in FIG. 113C, the yellow developing container **8054** is positioned in the mounting and dismounting position. In this state, the yellow developing container **8054** can be mounted and dismounted via the developing container mounting and dismounting opening **8010e**, that is, the yellow developing container **8054** can be mounted to the mounting and dismounting section **8050d** or it can be dismounted from the mounting and dismounting section **8050d**.

It should be noted that after the power source of the printer **8010** has been turned on and an initialization operation has been performed, and before the printer **8010** forms an image, the developing container holding unit **8050** is positioned in the home position shown in FIG. 113D.

—Configuration of the Communication Unit—

The configuration of the communication unit provided in the developing container as well as the configuration for sending and receiving data is described next with reference to FIG. 114, FIG. 115 and FIG. 116. FIG. 114 is a plan view showing the configuration of the communication unit. FIG. 115 is a block diagram illustrating the internal configuration of the communication unit and the send/receive section. FIG. 116 is a diagram illustrating the information stored in a memory cell **8054h** of the communication unit **8054a**.

Communication units are attached respectively to the developing containers **8051**, **8052**, **8053**, and **8054**, but since the configuration of the communication units attached to the developing containers and the positions at which the communication units are attached to the developing container main units are the same for all developing containers, the following is an explanation taking the communication unit **8054a** attached to the yellow developing container **8054** as an example.

When the yellow developing container **8054** is mounted to the mounting and dismounting section **8050d**, the communication unit **8054a** can communicate with the antenna unit **8124** on the side of the printer **8010** in a noncontacting manner. As mentioned above, the yellow developing container **8054** is moved by the movement of the mounting and dismounting section **8050d**. When the yellow developing container **8054** has been moved to the communication position, which is different from the developing position, the communication unit **8054a** communicates in a noncontacting manner with the antenna unit **8124** with which the printer **8010** is provided. The communication unit **8054a** is provided inward of the antenna unit **8124** in radial direction with respect to the center of the rotation shaft **8050e** of the developing container holding unit **8050**.

The communication unit **8054a** includes a thin plate-shaped substrate **8054i** serving as a substrate made of a thin plate-shaped piece of plastic that is flexible in its longitudinal direction, an antenna **8054d** serving as a first antenna made by arranging copper foil in a rectangular planar coil shape, antenna terminals **8054j** provided on both end portions of the antenna, a non-contact IC chip **8054b** including a memory and serving as an element for communicating with an external antenna, two coupling sections **8054k** made of aluminum that connect the chip terminals of the non-contact IC chip **8054b** with the antenna terminals **8054j**, and a film-shaped protective sheet **8054m** covering these elements, sandwiching them together with the thin plate-shaped substrate **8054i**.

As shown in FIG. 114, one antenna terminal **8054j** of the antenna **8054d** is arranged at one end side in the longitudinal direction of the rectangular thin plate-shaped substrate **8054i**, the antenna **8054d** is wrapped about ten times in a coil shape along the outer shape of the thin plate-shaped substrate **8054i**, and the other antenna terminal **8054j** is provided to the inner side of the antenna **8054d**. The outer antenna terminal **8054j** and the inner antenna terminal **8054j** are both provided on the same side in the longitudinal direction of the thin plate-shaped substrate **8054i**. On the thin plate-shaped substrate **8054i**, the ten copper foil structures of the antenna **8054d** are lined up next to each other along the vertical and horizontal edges of the rectangular shape, and are divided into five each at one corner portion on that end portion side of the thin plate-shaped substrate **8054i** where the antenna terminals **8054j** are provided, the non-contact IC chip **8054b** being arranged between these. Furthermore, two coupling sections **8054k** connecting chip terminals (not shown in the drawings) provided on the non-contact IC chip **8054b** with the antenna terminals **8054j** are provided, respectively straddling five

copper foil structures. That is to say, on the thin plate-shaped substrate **8054i**, the non-contact IC chip **8054b**, two antenna terminals **8054j**, and two coupling sections **8054k** are provided on a one end side in longitudinal direction, and the copper foil structures serving as the antenna **8054d** are guided around the remaining region, except for the center.

As shown in FIG. 108, the communication unit **8054a** is provided between the positioning pin **8588** and the coupling member **8590**, on the downstream side from the center in the longitudinal direction of the yellow developing container main unit on the side of the positioning pin **8588**, that is, on the downstream side from the center with respect to the direction in which the yellow developing container **8054** is mounted. In this situation, the communication unit **8054a** is arranged such that the end portion side where the non-contact IC chip **8054b** is provided is arranged on the upstream side of the communication unit **8054a** with respect to the mounting direction.

Moreover, the communication unit **8054a** is attached to an outer surface **8543** of the housing **8540**, which is provided extending in the longitudinal direction of the housing **8540**. Here, the outer surface **8543** refers to the part of the housing **8540** corresponding to the dash-dotted line in FIG. 109. It should be noted that this outer surface **8543** includes a circularly arc-shaped surface **8543a**, whose cross section through a perpendicular plane that is perpendicular to the longitudinal direction of the housing **8540** is circularly arc-shaped. This circularly arc-shaped surface **8543a** is arranged such that its circular arc extends along the rotation direction of the developing container holding unit **8050** when the yellow developing container **8054** is mounted to the mounting and dismounting section **8050d**. As shown in FIG. 109, the communication unit **8054a** is attached at a position of the circularly arc-shaped surface **8543a** that is furthest removed from the developing roller **8510**.

FIG. 117 is a diagram illustrating the antenna unit **8124**. FIG. 118 is a diagram illustrating how the antenna unit is attached to a holder. FIG. 119 is a diagram illustrating the arrangement of the antenna unit in a first working example of the ninth embodiment.

The antenna unit **8124** provided on the side of the printer **8010** includes a substrate **8124a** that is formed on a plate material made of resin, an antenna **8124b** serving as a second antenna that is made of copper foil wrapped in a planar coil shape along the outer shape of the substrate **8124a**, substantially the same as in the communication unit **8054a**, antenna terminals **8124c** provided at the end portions of the antenna **8124b**, and a film-shaped protective sheet **8124d**. Furthermore, the two antenna terminals **8124c** are each connected to a wire **8124e** and connected to the control unit **8100** via the communication control module **8123**. Here, the antenna unit **8124** of the present embodiment is configured having a protective sheet **8124d**, but it is not necessarily required to provide the protective sheet **8124d**.

The communication control module **8123** is an antenna driving circuit board for controlling the timing of the communication between the communication unit **8054a** and the antenna **8124b** and the writing of information into the non-contact IC chip **8054b**, as well as the reading of information from the non-contact IC chip **8054b**, and the exchange of this information between the communication unit **8054a** and the unit controller **8102**. Moreover, when the mounted yellow developing container **8054** is arranged in the communication position, the antenna **8054d** of the communication unit **8054a** and the antenna **8124b** of the antenna unit **8124** are arranged along the radial direction of a circle given by the rotation trajectory of the developing container holding unit **8050**, with

an inner wall plate **8066a** of the exhaust duct **8066** arranged between them. In the first working example shown in FIG. 119, the antenna unit **8124** is fixed with a holder **8125** made of resin to the inner wall plate **8066a** of the exhaust duct **8066** made of resin.

The holder **8125** is box-shaped, covering the surroundings of the antenna unit **8124** as well as the sides of the substrate **8124a** and open on one side, and is arranged such that the antenna **8124b** faces the outer side from the open side. At the edges of the open sides of the holder **8125**, flexible tongues **8125b** protruding toward the inside are provided on opposing side walls **8125a**. The antenna unit **8124** is accommodated inside the box-shaped holder **8125** and is held there by the tongues **8125b**. That is to say, the antenna unit **8124** is held only by the holder **8125** made of resin, so that metal components such as screws are not required to fasten the antenna unit **8124**.

If the communication unit **8054a** and the antenna unit **8124** are in a predetermined positional relationship, for example, if they are within a distance of 10 mm of one another, then information can be exchanged in a noncontacting manner between the two. The communication unit **8054a** is overall very compact and thin, and is adhesive on one of its sides and can be adhered to an object as a seal. It is also called a memory tag, for example, and is commercially available in various forms.

As shown in FIG. 115, the non-contact IC chip **8054b** includes a resonance capacitor **8054c**, a rectifier **8054e**, a signal analysis section RF (Radio Frequency) **8054f**, a controller **8054g**, and the memory cell **8054h**. The memory cell **8054h** is a nonvolatile memory that can be electrically read and written, such as an NAND flash ROM, and is capable of storing information that has been written on it and reading stored information from the outside.

The antenna **8054d** of the communication unit **8054a** and the antenna unit **8124** communicate wirelessly with one another, so that information stored in the memory cell **8054h** can be read and information can be written to the memory cell **8054h**. Also, the high-frequency signals that are generated by the communication control module **8123** of the printer **8010** are induced as a high-frequency magnetic field via the antenna unit **8124**. This high-frequency magnetic field is absorbed via the antenna **8054d** of the communication unit **8054a** and is rectified by the rectifier **8054e**, thus serving as a DC power source for driving the circuits in the non-contact IC chip **8054b**.

The memory cell **8054h** of the communication unit **8054a** stores various types of information, as shown in FIG. 116. The address 00H stores unique ID information for each communication unit, such as the serial number of the communication unit, the address 01H stores the date when the yellow developing container **8054** was manufactured, the address 02H stores information for specifying the destination of the yellow developing container **8054**, the address 03H stores information for specifying the manufacturing line on which the yellow developing container **8054** was manufactured, the address 04H stores information for specifying models with which the yellow developing container **8054** is compatible, the address 05H stores remaining toner amount information as information indicating the amount of toner that is contained in the yellow developing container **8054**, and the address 06H and subsequent regions also store information as appropriate.

The ID information that is stored in the memory cell **8054h** of the communication unit **8054a** can be written at the time that the storage communication unit is manufactured in the

factory. The printer **8010** can read this ID information to identify the individual communication units **8054a**, **8051a**, **8052a**, and **8053a**.

It should be noted that it is also possible to let the antenna unit **8124** communicate wirelessly with the communication unit **8054a** not only when the developing container holding unit **8050** is standing still but also when the developing container holding unit **8050** is moving. That is, the antenna unit **8124** may be able to communicate wirelessly with the communication unit **8054a** even when the communication unit **8054a** is moving.

====Communication Distance and Communication Region of Communication Units and Antenna Unit====

FIG. 120 is a cross-sectional view, taken from a direction perpendicular to the mounting direction, illustrating the communication distance and the communication region of the communication units and the antenna unit. FIG. 121 is a cross-sectional view, taken from a direction parallel to the mounting direction, illustrating the communication distance and the communication region of the communication units and the antenna unit.

As shown in these drawings, the communication units **8051a**, **8052a**, **8053a**, and **8054a** and the antenna unit **8124** are spaced apart by a communication distance **L**. The communication units **8051a**, **8052a**, **8053a**, and **8054a** are provided, respectively, on the developing containers **8051**, **8052**, **8053**, and **8054**. They are held by the developing container holding unit **8050** and are moved by rotating the developing container holding unit **8050** around its rotation shaft **8050e**. For this reason, the antenna unit **8124**, which is provided on the side of the printer **8010**, is arranged at a position where it does not come into contact with the portion protruding furthest outward when the developing container holding unit **8050** holding the developing containers **8051**, **8052**, **8053**, and **8054** rotates. On the other hand, rolls **8574** are provided on the shaft sections **8510b** of the developing roller **8510** of the developing container, such that the developing roller **8510** and the photoconductor **8020** face each other at a predetermined distance. That is to say, the rolls **8574** are the only components that come in contact with the printer **8010**. For this reason, the communication units **8051a**, **8052a**, **8053a**, and **8054a** are disposed inward from the outer circumference of the rolls **8574**, that is, closer to the center of the rotation shaft **8050e**, and the antenna unit **8124** is disposed outward from the outer circumference of the rolls **8574**, that is, on the side that is further away from the center of the rotation shaft **8050e**.

The communication units **8051a**, **8052a**, **8053a**, and **8054a** and the antenna unit **8124** are arranged such that they face each other at the above-mentioned communication position, preferably spaced apart at a communication distance **L** of, for example, 10 mm, at which satisfactory communication is possible. Moreover, the communication units **8051a**, **8052a**, **8053a**, and **8054a** do not include a power source, so that electric power is supplied to them through carrier waves from the antenna unit **8124**. That is to say, electric power as well as signals are transmitted to the communication units **8051a**, **8052a**, **8053a**, and **8054a** through electromagnetic induction occurring between the planar coil-shaped antennas **8054d** and **8124b** with which the communication units **8051a**, **8052a**, **8053a**, and **8054a** and the antenna unit **8124** are respectively provided. For this reason, when the communication units **8051a**, **8052a**, **8053a**, and **8054a** and the antenna unit **8124** communicate, a magnetic flux occurs around the copper foils of the antennas **8051d**, **8052d**, **8053d**, **8054d**, and **8124b**. This magnetic flux occurring at the antenna unit **8124b** of the antenna

unit **8124** then has to reach at least the antennas **8051d**, **8052d**, **8053d**, and **8054d** of the communication units **8051a**, **8052a**, **8053a**, and **8054a**, which are removed by at least the communication distance **L**. That is to say, for the communication units **8051a**, **8052a**, **8053a**, and **8054a** and the antenna unit **8124** to communicate, it is necessary that magnetic flux can be generated in a region of the distance **L** around the copper foils of the antennas **8051d**, **8052d**, **8053d**, **8054d**, and **8124b** (referred to as "communication region **M**" below). Considering the precision of the components of the communication units **8051a**, **8052a**, **8053a**, and **8054a** and the antenna unit **8124** or attachment errors when attaching components to the printer **8010**, it is preferable that the radius **L**, which defines the communication distance **L** and the communication region **M**, is set to such a distance that favorable communication conditions can be ensured.

In the case of this embodiment, around the communication units **8051a**, **8052a**, **8053a**, and **8054a** and the antenna unit **8124**, a region of the distance **L** from the center of the copper foil constituting the antennas of the communication units and the antenna of the antenna unit becomes the communication region **M**, as shown in FIG. 120 and FIG. 121.

Now, if there are conductive members within this communication region **M**, then the magnetic flux occurring in the antenna **8124b** passes through the conductive members, so that eddy currents flow through these conductive members with the magnetic flux at the axial center and the carrier wave is attenuated significantly. For this reason, the communication region **M** of this embodiment is set to such a region that no other conductive members besides the communication units **8051a**, **8052a**, **8053a**, **8054a**, the antenna unit **8124**, and the wires **8124e** are present within this communication region **M**.

====Arrangement of Exhaust Duct and Antenna Unit====

The following is, first of all, an explanation of the exhaust duct **8066** with which the antenna unit **8124** is provided. FIG. 122 is a diagram of the exhaust duct, taken from A3 in FIG. 103.

The exhaust duct **8066**, whose opening **8066b** on the inner side of the printer **8010** faces the photoconductor unit **8075**, extends along the outer circumference of the developing container holding unit **8050**, and is configured to exhaust air inside the printer that is sucked by an exhaust fan **8062** provided on the lower side of the printer **8010** to the outside. A portion of the wall on the outer circumferential side of the exhaust duct **8066** is constituted by the shielding member **8098a** of the power source unit **8098** and the stay **8010g**. Furthermore, the inner wall plate **8066a** on the side of the developing container holding unit **8050**, which constitutes the exhaust duct **8066**, is made of resin.

Inside the exhaust duct **8066**, a filter **8064** for scavenging toner, dust and the like included in the sucked air is arranged above the developing container holding unit **8050**. The opening **8066b** of the exhaust duct **8066** on the inner side of the printer **8010** has about the same width as the length of the photoconductor **8020** in longitudinal direction, and this width continues to a position where the filter **8064** is accommodated. The width of the exhaust duct **8066** on the side of the exhaust fan **8062** is narrower than the filter **8064**. The antenna **8124** and the communication control module **8123** for communicating with the communication units **8051a**, **8052a**, **8053a**, and **8054a** provided on the developing containers are provided at a part where the width of the exhaust duct **8066** has become narrower. That is to say, upstream, with respect to the direction of the air flow, from an antenna placement part **8066d** where the antenna unit **8124** is arranged, the exhaust

duct **8066** has a part with a cross-sectional area that is larger than the cross-sectional area in a direction intersecting with the direction of the air flow at the antenna placement part **8066d**. Moreover, an exhaust-side opening **8066c** of the exhaust duct **8066** is connected to a suction port **8062a** of the exhaust fan **8062**, and an exhaust port **8062b** of the exhaust fan **8062** is directed toward the outside of the printer **8010** in a direction perpendicular to the mounting direction of the developing containers in the printer **8010**.

That is to say, with regard to the direction of the airflow within the exhaust duct **8066**, the opening **8066b** on the inner side of the printer, which is the most upstream side, follows in its longitudinal direction along the photoconductor **8020**, and is arranged in opposition to the photoconductor **8020**. Air inside the printer **8010** is sucked in from the opening **8066b**, which has a larger cross-sectional area than the cross-sectional area at the antenna placement part **8066d**. In this situation, also unnecessary toner near the developing containers **8051**, **8052**, **8053**, and **8054** is sucked in from the opening **8066b**. The air and the like that is sucked in is passed through the exhaust duct **8066** and reaches the filter **8064**, and when it passes through the filter **8064**, toner and the like mixed into the air is scavenged by the filter **8064**. The air that has passed through the filter **8064** flows to the downstream side while the speed of the air flow is accelerated due to the fact that the shape of the exhaust duct **8066** becomes narrower. The accelerated air flow passes along the antenna unit **8124**, which is provided inside the exhaust duct **8066** at the antenna placement part **8066d**. Thus, the antenna unit **8124** is cooled by the air flow. As the air that has passed the antenna placement part **8066d** is output from the exhaust-side opening **8066c** on the furthest downstream in the exhaust duct **8066**, it flows from the suction port **8062a** into the exhaust fan **8062** and is exhausted from the exhaust port **8062b** to the outside of the printer **8010**.

With the printer **8010** according to this first working example of the ninth embodiment, the exhaust duct **8066** provided inside the printer **8010** is a passageway of an air flow, so that the inside of the exhaust duct **8066** is cooled by the airflow. Therefore, also the antenna **8124b** of the antenna unit **8124** with which the exhaust duct **8066** is provided is cooled, so that a temperature increase of the antenna **8124b** is suppressed. That is to say, by providing the antenna **8124b** inside the exhaust duct **8066**, the antenna **8124b** is cooled directly by the air flow, so that it is possible to cool the antenna **8124b** efficiently. By suppressing an increase in temperature due to the cooling, it is possible to ensure favorable communication between the printer **8010** and the communication unit **8054a**.

Furthermore, with the printer **8010** according to the ninth embodiment, upstream of the antenna placement part **8066d**, there is a part having a cross-sectional area that is larger than the cross-sectional area in the direction perpendicular to the direction of the air flow at the antenna placement part **8066d**, for example the part where the filter **8064** is provided, so that the air flow within the exhaust duct **8066** is accelerated at the antenna placement part **8066d**. Therefore, the antenna **8124b** of the antenna unit **8124** provided at the antenna placement part **8066d** can be cooled more efficiently by the fast air flow.

Furthermore, the inner wall plate **8066a** of the exhaust duct **8066** is made of resin, that is, a non-conductive member, so that it is possible to ensure favorable communication through the antenna **8054d**, without blocking the antenna **8124b** with the exhaust duct **8066**. Therefore, by providing the antenna unit **8124** inside the exhaust duct **8066** in order to cool the antenna unit **8124**, it is possible to ensure favorable communication conditions, even when the inner wall plate **8066a** of

the exhaust duct **8066** is arranged between the antenna unit **8124** and the communication unit **8054a**.

Moreover, as a method for cooling the antenna unit **8124**, the exhaust duct **8066** for exhausting the air inside the printer **8010** to outside of the printer **8010** is used, so that it is possible to cool the antenna **8124b** by using the air flow generated by exhausting the air inside the printer **8010**, without providing a separate cooling device.

Moreover, the filter **8064** is provided upstream of the antenna unit **8124**, with respect to the direction of the air flow inside the exhaust duct **8066**, so that it is possible to prevent dirt, dust and the like inside the printer **8010** from adhering to the antenna unit **8124**. Now, if no filter **8064** is provided, and conductive material, such as iron powder is included in the dust, dirt and the like inside the printer **8010**, then there is the risk that favorable communication with the communication unit **8054a** through the antenna unit **8124** is not possible when this iron powder or the like adheres to the antenna unit **8124**. Since the filter **8064** is provided upstream of the antenna unit **8124**, iron powder and the like is prevented from adhering to the antenna **8124b**, and a favorable communication state is maintained.

Moreover, the printer **8010** according to the first working example of the ninth embodiment is a laser printer, so that for example toner is used as the developer. Therefore, the exhaust duct **8066** and the filter **8064** are typically provided inside the printer **8010**, so that no toner is scattered, but by using this exhaust duct **8066** to cool the antenna unit **8124**, it is possible to realize favorable communication via the communication unit **8054a** and the antenna unit **8124**, while preventing the scattering of the toner.

Moreover, in the printer **8010** according to this first working example of the ninth embodiment, also the communication control module **8123** connected to the antenna **8124b** is provided inside the exhaust duct **8066**, so that it is possible to cool also the communication control module **8123** with the air flow inside the exhaust duct **8066**.

FIG. 123 is a diagram showing a second working example of the ninth embodiment. In the second working example shown in the diagram, flexible tongues **8066e** protruding from the inner wall plate **8066a** of the exhaust duct **8066** into the exhaust duct **8066** is provided, and the antenna unit **8124** is directly fixed to an inner wall surface **8066f** by these tongues **8066e**. Therefore, it is not necessary to provide a separate member for fixing the antenna unit **8124**. That is to say, it is possible to directly expose the antenna unit **8124** to the air flow and cool it efficiently, while reducing the number of parts and the number of man-hours for assembly. In this case, the antenna unit **8124** does not protrude deeply into the exhaust duct **8066** as in the first working example, so that it is less likely to obstruct the air flow, but since only one side of the antenna unit **8124** can be exposed to the air flow, the cooling efficiency is lower than in the first working example.

FIG. 124 is a diagram showing a third working example. In the third working example shown in the diagram, flexible tongues **8066e** protruding in a direction out of the exhaust duct **8066** from the inner wall plate **8066a** of the exhaust duct **8066** are provided, and the antenna unit **8124** is directly fixed to the inner wall plate **8066a** by these tongues **8066e**. Therefore, as in the second working example, it is not necessary to provide a separate member for fixing the antenna unit **8124**, and it is possible to cool the antenna unit **8124** while reducing the number of parts and the number of man-hours for assembly. However, in the third working example, the antenna unit **8124** is provided on an outer wall surface **8066g** of the exhaust duct **8066**, so that the antenna unit **8124** is cooled via the inner wall plate **8066a** of the exhaust duct **8066**. There-

fore, the efficiency with which the antenna unit **8124** is cooled is lower than in the first working example and the second working example. On the other hand, in comparison to the first working example and the second working example, in which the antenna unit **8124** is provided inside the exhaust duct **8066**, the inner wall plate **8066a** is present between the antenna unit **8124** and the communication unit **8054a**, so that it is possible to arrange the antenna unit **8124** and the communication unit **8054a** closer to each other than in the first working example and the second working example. Thus, it is possible to arrange the antenna unit **8124** and the communication unit **8054** at a distance at which favorable communication is possible, and furthermore to achieve favorable communication by cooling the antenna **8124b** via the exhaust duct **8066**.

In the present embodiment, an example was shown in which both the antenna unit **8124** and the communication control module **8123** are arranged in the exhaust duct **8066**, but it is also possible to arrange only the antenna unit **8124** in the exhaust duct **8066**. Moreover, the antenna unit **8124** was arranged in the exhaust duct **8066**, but as long as it is a part at which an air flow is generated, it is also possible to arrange it in a suction duct, or to arrange it in a duct that is provided for cooling a specified unit, such as the exposing unit **8040**.

Other Embodiments

An image forming apparatus or the like according to this invention was explained by way of the foregoing embodiment, but the foregoing embodiment of the invention is merely for the purpose of elucidating the present invention and is not to be interpreted as limiting the present invention. The invention can of course be altered and improved without departing from the gist thereof and equivalents are intended to be embraced therein.

In the foregoing embodiment, an intermediate image transfer type full-color laser beam printer was described as an example of the image forming apparatus, but the present invention can also be applied to various other types of image forming apparatuses, such as full-color laser beam printers that are not of the intermediate image transfer type, monochrome laser beam printers, copying machines, and facsimiles.

Also, in the foregoing embodiment, the photoconductor, which is an image bearing member, was explained as having a photoconductive layer on the outer circumferential surface of a hollow cylindrical conductive member, but there is no limitation to this. For example, it may also be a so-called photoconductive belt, in which a photoconductive layer is provided on the surface of a belt-shaped photoconductive member.

Furthermore, in the foregoing embodiment, as shown in FIG. 103 for example, the mounting and dismounting sections **8050a**, **8050b**, **8050c**, and **8050d** are movable, and when the developing containers **8051**, **8052**, **8053**, and **8054** are mounted to the mounting and dismounting sections and are moved to the developing position through the movement of the mounting and dismounting sections, then the latent image borne on the photoconductor **8020** (image bearing member) provided in the printer **8010** is developed. Moreover, the communication units **8051a**, **8052a**, **8053a**, and **8054a** communicate in a noncontacting manner with the printer **8010** when the developing containers **8051**, **8052**, **8053**, and **8054** have been moved to the communication position, which is different from the developing position. However, there is no limitation to this. For example, it is also possible to let the developing containers not move at all.

However, if the developing containers **8051**, **8052**, **8053**, and **8054** move together with the movement of the mounting and dismounting sections **8050a**, **8050b**, **8050c**, and **8050d**, then the relative position between the developing container main units and the coupling member **8590** changes more easily when the developing containers are positioned in the communication position than in the case that the developing containers do not move, so that there is a greater risk that the distance between the printer **8010** and the elements **8051a**, **8052a**, **8053a**, and **8054a** changes. Therefore, the effect of providing the communication unit on the one end side in the longitudinal direction of the developing container main units, that is, the effect that developing containers can be realized that can communicate properly with the printer **8010** is more advantageous in the case that the developing containers move together with the movement of the mounting and dismounting sections. For this reason, the above-described embodiment is more preferable.

Furthermore, in the foregoing embodiment, as shown in FIG. 110, the developing container main units include a developing roller **8510** (developer bearing member) for bearing toner **T** (developer) and developing the latent image borne on the photoconductor **8020** with toner **T**, and rolls **8574** (distance holding members) that are provided at both end portions in the longitudinal direction of the developing rollers **8510** and that are for holding a distance between the photoconductor **8020** and the developing roller **8510** by coming into contact with the photoconductor **8020**. Moreover, when the developing containers **8051**, **8052**, **8053**, and **8054** are moved to the developing position, the rolls **8574** hold this distance by coming into contact with the photoconductor **8020**. However, there is no limitation to this.

Furthermore, in the above-described embodiment, as shown in FIG. 108, the developing container main unit is supported by the housing **8540** at both end portions in the longitudinal direction, and is provided with the developing roller **8510** for bearing the toner **T** and developing the latent image borne on the photoconductor **8020** with the toner **T**. Moreover, as shown in FIG. 109, the outer surface **8543** of the housing **8540** is provided with a circularly arc-shaped surface **8543a**, whose cross section through a perpendicular plane that is perpendicular to the longitudinal direction of the housing **8540** is circularly arc-shaped. As shown in FIG. 109, the communication units **8051a**, **8052a**, **8053a**, and **8054a** are attached at positions of the circularly arc-shaped surface **8543a** that are furthest removed from the developing rollers **8510**. However, there is no limitation to this. For example, it is also possible that the communication units are attached at positions of the circularly arc-shaped surface **8543a** that are close to the developing rollers **8510**.

However, if the communication units **8051a**, **8052a**, **8053a**, and **8054a** are attached at the positions of the circularly arc-shaped surface **8543a** that are furthest removed from the developing rollers **8510**, then it can be prevented that the toner **T** borne on the developing rollers **8510** is scattered and adheres to the communication units, so that the communication units can communicate more properly with the printer **8010**. For this reason, the above-described embodiment is more preferable.

==Configuration of Image Forming System Etc.==

Next, an embodiment of an image forming system serving as an example of an embodiment of the present invention is described with reference to the drawings.

FIG. 125 is an explanatory diagram showing the external configuration of an image forming system. An image forming

185

system 8700 is provided with a computer 8702, a display device 8704, a printer 8010, input devices 8708 and reading devices 8710.

In this embodiment, the computer 8702 is contained within a mini-tower type housing, but there is no limitation to this. A CRT (cathode ray tube), plasma display, or liquid crystal display device, for example, is generally used as the display device 8704, but there is no limitation to this. As the printer 8010, the printer described above is used. In this embodiment, the input devices 8708 are a keyboard 8708A and a mouse 8708B, but there is no limitation to these. In this embodiment, a flexible disk drive device 8710A and a CD-ROM drive device 8710B are used as the reading devices 710, but there is no limitation to these, and it is also possible to use an MO (magneto-optical) disk drive device or a DVD (digital versatile disk), for example.

FIG. 126 is a block diagram showing the configuration of the image forming system shown in FIG. 125. An internal memory 8802 such as a RAM is provided within the casing containing the computer 8702, and furthermore an external memory such as a hard disk drive unit 8804 is provided.

In the above explanations, an example was given in which the image forming system is constituted by connecting the printer 8010 to the computer 8702, the display device 8704, the input devices 8708, and the reading devices 8710, but there is no limitation to this. For example, the image forming system may also be made of the computer 8702 and the printer 8010, and the image forming system does not have to be provided with any one of the display device 8704, the input devices 8708, and the reading devices 8710.

It is also possible that the printer 8010 has some of the functions or mechanisms of the computer 8702, the display device 8704, the input devices 8708, and the reading devices 8710. For example, the printer 8010 may be configured so as to have an image processing section for carrying out image processing, a display section for carrying out various types of displays, and a recording media mounting and dismounting section into and from which recording media storing image data captured by a digital camera or the like are inserted and taken out.

As an overall system, the image forming system that is thus achieved is superior to conventional systems.

Overview of Image Forming Apparatus of Tenth Embodiment

Next, using FIG. 127 and FIG. 128, an overview of a laser beam printer (hereinafter, also referred to as "printer") 9010 serving as an example of an image forming apparatus is described. FIG. 127 is a diagram illustrating how the developing unit 9051 (9052, 9053, 9054) and the photoconductor unit 9075 are mounted to and dismounted from the printer main unit 9010a, which is an example of an image forming apparatus. FIG. 128 is a diagram showing the main structural components constituting the printer 9010. It should be noted that FIG. 128 is a diagram of a cross section taken perpendicular to the X direction in FIG. 127. Also, the vertical direction is indicated by arrows in FIG. 127 and FIG. 128, and for example, a paper supply tray 9092 is disposed at a lower part of the printer 9010 and a fixing unit 9090 is disposed at an upper part of the printer 9010.

<<Mounting and Dismounting Configuration>>

The developing unit 9051 (9052, 9053, 9054) and the photoconductor unit 9075 can be mounted to and dismounted from the printer main unit 9010a. The printer 9010 is consti-

186

tuted by mounting the developing unit 9051 (9052, 9053, 9054) and the photoconductor unit 9075 to the printer main unit 9010a.

The printer main unit 9010a has a first opening and closing cover 9010b that can be opened and closed, a second opening and closing cover 9010c that can be opened and closed and that is provided more inward than the first opening and closing cover 9010b, a photoconductor unit mounting and dismounting opening 9010d through which the photoconductor unit 9075 is mounted and dismounted, and a developing unit mounting and dismounting opening 9010e through which the developing unit 9051 (9052, 9053, 9054) is mounted and dismounted.

Here, by opening the first opening and closing cover 9010b, the user can mount and dismount the photoconductor unit 9075 with respect to the printer main unit 9010a through the photoconductor unit mounting and dismounting opening 9010d. The photoconductor unit 9075 is mounted to the printer main unit 9010a by inserting it into the printer main unit 9010a.

Further, by opening the second opening and closing cover 9010c, the user can mount and dismount the developing unit 9051 (9052, 9053, 9054) with respect to the printer main unit 9010a through the developing unit mounting and dismounting opening 9010e. The developing unit 9051 (9052, 9053, 9054) is mounted to the printer main unit 9010a by inserting it into the printer main unit 9010a.

<<Overview of the Printer 9010>>

The following explains an overview of the printer 9010 in which the developing unit 9051 (9052, 9053, 9054) and the photoconductor unit 9075 are mounted to the printer main unit 9010a.

As shown in FIG. 128, the printer 9010 of this embodiment has a charging unit 9030, an exposing unit 9040, a YMCK developing device 9050, a primary image transfer unit 9060, an intermediate image transfer member 9070, and a cleaning blade 9076, arranged along the rotation direction of the photoconductor 9020. It further includes a secondary image transfer unit 9080, a fixing unit 9090, a display unit 9095 made of a liquid crystal panel for constituting means for notifying the user, for example, and a control unit 9100 (FIG. 129) for controlling these units, for example, so as to control the operation of the printer 9010.

The photoconductor 9020 has a hollow cylindrical conductive base and a photoconductive layer formed on the outer circumferential surface of the conductive base, and is rotatable around its center axis. In the present embodiment, the photoconductor 9020 rotates clockwise, as indicated by the arrow in FIG. 128.

The charging unit 9030 is a device for charging the photoconductor 9020. The exposing unit 9040 is a device for forming a latent image on the charged photoconductor 9020 by irradiating a laser beam thereon. The exposing unit 9040 includes, for example, a semiconductor laser, a polygon mirror, and an F-θ lens, and irradiates a modulated laser beam onto the charged photoconductor 9020 in accordance with image signals that have been input from a host computer not shown in the drawings, such as a personal computer or a word processor.

The YMCK developing device 9050 has a rotary 9055 that serves as a rotating member, and four developing units mounted to the rotary 9055. The rotary 9055 is capable of rotation, and is provided with four mounting and dismounting sections 9055b, 9055c, 9055d, and 9055e with respect to which the four developing units 9051, 9052, 9053 and 9054, respectively, can be mounted and dismounted through the

developing unit mounting and dismounting opening 9010e. The black developing unit 9051, which accommodates black (K) toner, can be mounted to and dismounted from the mounting and dismounting section 9055b, the magenta developing unit 9052, which accommodates magenta (M) toner, can be mounted to and dismounted from the mounting and dismounting section 9055c, the cyan developing unit 9053, which accommodates cyan (C) toner, can be mounted to and dismounted from the mounting and dismounting section 9055d, and the yellow developing unit 9054, which accommodates black yellow (Y) toner, can be mounted to and dismounted from the mounting and dismounting section 9055e.

By rotating, the rotary 9055 moves the four developing units 9051, 9052, 9053, and 9054 that are mounted to the mounting and dismounting sections 9055b, 9055c, 9055d, and 9055e, respectively. That is, the rotary 9055 rotates the four mounted developing units 9051, 9052, 9053, and 9054 about a central shaft 9055a while maintaining their positions relative to one another. The developing units 9051, 9052, 9053, and 9054 are selectively brought into opposition with the latent image formed on the photoconductor 9020, and develop the latent image on the photoconductor 9020 with the toner, which is an example of a developer, contained in the developing units 9051, 9052, 9053, and 9054. It should be noted that the developing units are described in detail later.

The primary image transfer unit 9060 is a device for transferring a single color toner image formed on the photoconductor 9020 to the intermediate image transfer member 9070. When the four toner colors are successively transferred over one another, a full color toner image is formed on the intermediate image transfer member 9070.

The intermediate image transfer member 9070 is a layered endless belt made by providing a tin vapor deposition layer on the surface of a PET film and forming a semiconductive coating on its surface. The intermediate image transfer member 9070 is driven to rotate at substantially the same circumferential speed as the photoconductor 9020. A read sensor RS for synchronization is provided near the intermediate image transfer member 9070. The read sensor RS for synchronization is a sensor for detecting a reference position of the intermediate image transfer member 9070, and obtains a synchronization signal Vsync in the sub-scanning direction, which is perpendicular to the main scanning direction. The read sensor RS for synchronization has a light-emitting section for emitting light and a light-receiving section for receiving light. Light that is emitted from the light-emitting section passes through a hole formed at a predetermined position of the intermediate image transfer member 9070, and when light is received by the light-receiving section, the read sensor RS for synchronization generates a pulse signal. One pulse signal is generated for each revolution of the intermediate image transfer member 9070.

The secondary image transfer unit 9080 is a device for transferring a single color toner image or a full color toner image formed on the intermediate image transfer member 9070 to a recording medium such as paper, film, or cloth.

The fixing unit 9090 is a device for fusing the single color toner image or the full color toner image that has been transferred to the recording medium on the recording medium, such as paper, making it a permanent image.

The cleaning blade 9076 is made of rubber and is in contact with the surface of the photoconductor 9020. The cleaning blade 9076 scrapes off and removes toner remaining on the photoconductor 9020, after the toner image has been transferred to the intermediate image transfer member 9070 by the primary image transfer unit 9060.

The control unit 9100 is made of a main controller 9101 and a unit controller 9102, as shown in FIG. 129. An image signal is input into the main controller 9101, and in accordance with a command based on this image signal, the unit controller 9102 controls the various units, for example, to form the image.

The photoconductor unit 9075 is arranged between the primary image transfer unit 9060 and the exposing unit 9040, and includes the photoconductor 9020, the charging unit 9030, the cleaning blade 9076, a waste toner containing section 9076a containing toner that has been scraped off by the cleaning blade 9076, a housing 9075b, and a memory unit 9075a that is provided in this housing 9075b. The memory unit 9075a is capable of wireless communication with a main unit-side antenna 9124a for the photoconductor unit, with which the printer main unit 9010a is provided.

—Operation of the Printer 9010—

The operation of the printer 9010 configured as above is described below, referring to other structural components thereof as well.

First, when an image signal from a host computer not shown in the drawings is input to the main controller 9101 of the printer 9010 via an interface (I/F) 9112, the photoconductor 9020 and the intermediate image transfer member 9070 are rotated under the control of the unit controller 9102 based on a command from the main controller 9101. Then, the reference position of the intermediate image transfer member 9070 is detected by the read sensor RS for synchronization, and a pulse signal is output. This pulse signal is sent to the unit controller 9102 via a serial interface 9121. The unit controller 9102 controls the following operation, taking the pulse signal that is received as a reference.

While rotating, the photoconductor 9020 is successively charged by the charging unit 9030 at a charging position. The region of the photoconductor 9020 that has been charged is brought to an exposure position through rotation of the photoconductor 9020, and a latent image corresponding to image information of a first color, for example yellow Y, is formed at that region by the exposing unit 9040.

The latent image formed on the photoconductor 9020 is brought to a developing position through the rotation of the photoconductor 9020, and is developed with yellow toner by the yellow developing unit 9054. Thus, a yellow toner image is formed on the photoconductor 9020.

The yellow toner image that is formed on the photoconductor 9020 is brought to the primary image transfer position through rotation of the photoconductor 9020 and is transferred to the intermediate image transfer member 9070 by the primary image transfer unit 9060. At this time, a primary image transfer voltage of a polarity that is opposite the toner charge polarity is applied to the primary image transfer unit 9060. It should be noted that, during this process, the photoconductor 9020 and the intermediate image transfer member 9070 are in contact, whereas the secondary image transfer unit 9080 is kept separated from the intermediate image transfer member 9070.

The above process is repeated for a second color, a third color, and a fourth color, transferring different color toner images corresponding to various image signals over one another onto the intermediate image transfer unit 9070. Thus, a full color toner image is formed on the intermediate image transfer member 9070. The full color toner image that is formed on the intermediate image transfer member 9070 is brought to the secondary image transfer position through the rotation of the intermediate image transfer member 9070 and is transferred to a recording medium by the secondary image

transfer unit 9080. It should be noted that the recording medium is carried from the paper supply tray 9092 to the secondary image transfer unit 80 via a paper supply roller 9094 and registration rollers 9096. Also, when performing the image transfer operation, the secondary image transfer unit 9080 is pressed against the intermediate image transfer member 9070 while applying a secondary image transfer voltage to it.

The fixing unit 9090 heats and applies pressure to the full color toner image that has been transferred to the recording medium, thus fusing it to the recording medium.

On the other hand, after the photoconductor 9020 has passed the primary image transfer position, the toner adhering to its surface is scraped off by the cleaning blade 9076, and it is provided with a charge for forming the next latent image. The toner that is wiped away is collected in the waste toner containing section 9076a.

—Overview of the Control Unit—

The configuration of the control unit 9100 is described next, with reference to FIG. 129. FIG. 129 is a block diagram showing the control unit 9100 provided in the printer 9010.

The main controller 9101 of the control unit 9100 is connected to a host computer via an interface 9112, and is provided with an image memory 9113 for storing image signals that it receives from this host computer.

The unit controller 9102 of the control unit 9100 is electrically connected to the various units (the charging unit 9030, the exposing unit 9040, the primary image transfer unit 9060, the photoconductor unit 9075, the secondary image transfer unit 9080, the fixing unit 9090, and the display unit 9095) and the YMCK developing device 9050. Receiving signals from the sensors provided in these components, the unit controller 9102 controls these units and the YMCK developing device 9050 based on signals input from the main controller 9101 as it detects the state of these units and the YMCK developing device 9050. As the structural components for driving these units and the YMCK developing device 9050, FIG. 129 shows a photoconductor unit drive control circuit, a charging unit drive control circuit, an exposing unit drive control circuit, a YMCK developing device drive control circuit, a primary image transfer unit drive control circuit, a secondary image transfer unit drive control circuit, a fixing unit drive control circuit, and a display unit drive control circuit.

Also, the CPU 9120 provided in the unit controller 9102 is connected to a non-volatile storage element (hereinafter, also referred to as main unit-side memory 9122) such as a serial EEPROM via the serial interface (I/F) 9121.

Moreover, the CPU 9120 is capable of wirelessly communicating with later-described memory units 9051a, 9052a, 9053a, and 9054a, which are respectively provided in the developing units 9051, 9052, 9053, and 9054, via the serial interface 9121, a send-receive circuit 9123, and a main unit-side antenna 9124b for the developing units. The CPU 9120 is further capable of wirelessly communicating with the memory unit 9075a provided in the photoconductor unit 9075 via the serial interface 9121, the send-receive circuit 9123 and a main unit-side antenna 9124a for the photoconductor unit. During wireless communication, the main unit-side antenna 9124b for the developing units writes information into the memory units 9051a, 9052a, 9053a, and 9054a provided in the developing units 9051, 9052, 9053, and 9054, respectively. The main unit-side antenna 9124b for the developing units is also capable of reading information from the memory units 9051a, 9052a, 9053a, and 9054a provided in the developing units 9051, 9052, 9053, and 9054, respectively. During wireless communication, the main unit-side antenna 9124a

for the photoconductor unit writes information into the memory unit 9075a provided in the photoconductor unit 9075. The main unit-side antenna 9124a for the photoconductor unit can also read information from the memory unit 9075a provided in the photoconductor unit 9075.

—Overview of the Developing Units—

An overview of the developing units is provided next using FIG. 130 to FIG. 137. FIG. 130 is a cross-sectional view showing the main structural components of the black developing unit 9051. FIG. 131 is a perspective view of the black developing unit 9051, taken from the side of the developing roller 9510. FIG. 132 is a perspective view showing an arrangement in which a label 9580 is removed from the black developing unit 9051 shown in FIG. 131. FIG. 133 is an exploded perspective view showing the positional relationship between the housing 9540, the memory unit 9051a, and the label 9580 of the black developing unit 9051. FIG. 134 is a cross-sectional diagrammatic view showing the positional relationship between the housing 9540, the memory unit 9051a, and the label 9580 of the black developing unit 9051. FIG. 135 to FIG. 137 are explained later. It should be noted that the cross-sectional view in FIG. 130 shows a cross section of the black developing unit 9051 taken along a plane that is perpendicular to the longitudinal direction shown in FIG. 131. Furthermore, in FIG. 130, the vertical direction is indicated by arrows, and, for example, the center axis of the developing roller 9510 is lower than the center axis of the photoconductor 9020. Also, in FIG. 130, the black developing unit 9051 is shown positioned at a developing position that is in opposition to the photoconductor 9020.

The rotary 9055 is provided with the black developing unit 9051 containing black (K) toner, the magenta (M) toner, the cyan developing unit 9052 containing magenta (M) toner, the cyan developing unit 9053 containing cyan (C) toner, and the yellow developing unit 9054 containing yellow (Y) toner. Since the configuration of each of the developing units is the same, only the black developing unit 9051 will be explained in the following.

As shown in FIG. 130 to FIG. 133, the black developing unit 9051 includes a housing 9540, a toner containing member 9530, a developing roller 9510, a toner supply roller 9550, a regulating blade 9560, a sealing member 9520, a memory unit 9051a, and a label 9580.

The housing 9540 is made by welding together an upper housing and a lower housing that are integrally molded. Inside the housing 9540, the toner containing member 9530 containing the toner T is formed. The toner containing member 9530 is divided by a regulating wall 9545 for partitioning the toner T, which protrudes inwards (in the vertical direction in FIG. 130) from the inner wall, into two toner containing sections, namely, a first toner containing section 9530a and a second toner containing section 9530b. The upper portions of the first toner containing section 9530a and the second toner containing section 9530b are in communication, and the movement of the toner T between them is regulated by the regulating wall 9545.

An opening 9541 that communicates with the outside of the housing 9540 is provided at the bottom portion of the first toner containing section 9530a. The toner supply roller 9550 is provided in the first toner containing section 9530a with its circumferential surface facing the opening 9541, and is rotatably supported on the housing 9540. Also, the developing roller 9510 is provided with its circumferential surface facing the opening 9541 from outside the housing 9540, and the developing roller 9510 is in contact with the toner supply roller 9550.

The developing roller **9510** bears toner T and carries it to the developing position opposite the photoconductor **9020**. The developing roller **9510** is made of aluminum, stainless steel or iron, for example, and if necessary, it can be subjected to nickel plating or chrome plating or the like. Moreover, as shown in FIG. 131, the developing roller **9510** is provided such that its longitudinal direction extends along the longitudinal direction of the black developing unit **9051**. Also, the developing roller **9510** can rotate around its center axis, and as shown in FIG. 130, it rotates in a direction (the counter-clockwise direction in FIG. 130) that is opposite to the direction in which the photoconductor **9020** rotates (the clockwise direction in FIG. 130). Its center axis is lower than the center axis of the photoconductor **9020**. As shown in FIG. 130, in a state where the black developing unit **9051** is in opposition to the photoconductor **9020**, there is a gap between the developing roller **9510** and the photoconductor **9020**. That is, the black developing unit **9051** develops the latent image formed on the photoconductor **9020** in a noncontacting manner. It should be noted that during the development of the latent image formed on the photoconductor **9020**, an alternating electric field is formed between the developing roller **9510** and the photoconductor **9020**.

The toner supply roller **9550** supplies toner T to the developing roller **9510**. This toner supply roller **9550** is made of polyurethane foam or the like, and is in contact with the developing roller **9510** in a state of elastic deformation. The toner supply roller **9550** is disposed at a lower part of the first toner containing section **9530a**, and the toner T contained in the first toner containing section **9530a** and the second toner containing section **9530b** is supplied to the developing roller **9510** by the toner supply roller **9550** at the lower part of the first toner containing section **9530a**. The toner supply roller **9550** is rotatable around its center axis. The center axis of the toner supply roller **9550** is lower than the central rotation axis of the developing roller **9510**. Also, the toner supply roller **9550** rotates in a direction (the clockwise direction in FIG. 130) that is opposite the rotation direction of the developing roller **9510** (the counterclockwise direction in FIG. 130). It should be noted that the toner supply roller **9550** not only has the function to supply toner T to the developing roller **9510**, but also the function to scrape off toner T that has remained on the developing roller **9510** after the development from the developing roller **9510**.

The regulating blade **9560** regulates the thickness of the toner T layer borne on the developing roller **9510**, and applies charge to the toner T borne on the developing roller **9510**. The regulating blade **9560** has a rubber part **9560a** and a rubber supporting part **9560b**. The rubber part **9560a** is made of silicone rubber or urethane rubber, for example, and the rubber supporting part **9560b** is a thin plate of phosphor bronze or stainless steel, for example, and has elasticity. The rubber part **9560a** is supported by the rubber support part **9560b**, and one end of the rubber supporting part **9560b** is fixed to a blade support metal plate **9562**. In this state, the rubber part **9560a** is pressed against the developing roller **9510** by the elastic force created by the bending of the rubber supporting part **9560b**.

Also, a blade backing member **9570** made of Moltopren or the like is provided on the side of the regulating blade **9560** that is opposite the side of the developing roller **9510**. The blade backing member **9570** prevents the toner T from entering in between the rubber supporting part **9560b** and the housing **9540** so as to stabilize the elasticity due to the bending of the rubber supporting part **9560b**, and presses the rubber part **9560a** against the developing roller **9510** by biasing the rubber part **9560a** toward the developing roller **9510**.

from directly behind the rubber part **9560a**. Consequently, the blade backing member **9570** increases the contact uniformity and the sealing properties of the rubber part **9560a** with respect to the developing roller **9510**.

The end of the regulating blade **9560** on the side opposite the side supported by the blade support metal plate **9562**, that is, its front end, is not in contact with the developing roller **9510**, and a portion thereof removed from this front end by a predetermined distance is in contact with the developing roller **9510** over a certain width. That is to say, the regulating blade **9560** does not come into contact with the developing roller **9510** at its edge but rather at a mid section thereof. Also, the regulating blade **9560** is disposed such that its front end is facing upstream with respect to the direction in which the developing roller **9510** rotates, and is in so-called counter contact. It should be noted that the contact position where the regulating blade **9560** contacts the developing roller **9510** is below the center axis of the developing roller **9510** and is below the center axis of the toner supply roller **9550**.

The sealing member **9520** prevents the toner T in the black developing unit **9051** from leaking out of the unit, and also collects toner T on the developing roller **9510**, after it has passed the developing position, into the developing unit without scraping it off. This sealing member **9520** is a seal made of polyethylene film or the like. The sealing member **9520** is supported by a seal support metal plate **9522**. Furthermore, a seal biasing member **9524** made of Moltopren or the like is provided on the side of the sealing member **9520** that is opposite to its developing roller **9510** side, and due to the elasticity of the seal biasing member **9524**, the sealing member **9520** is pressed against the developing roller **9510**. It should be noted that the contact position where the sealing member **9520** contacts the developing roller **9510** is above the center axis of the developing roller **9510**.

The memory unit **9051a** is provided on the housing **9540** described above. The memory unit **9051a** according to the present embodiment is a component having a small and thin rectangular shape. It is also referred to as "memory tag" and is commercially available in various forms.

This memory unit **9051a** has an adhesive surface **9572** (tacky surface) on its rear side, and is affixed to this housing **9540** by adhering this adhesive surface **9572** to the surface of the housing **9540**. More specifically, as shown in FIG. 133, the housing **9540** has an indentation **9540a**, and the memory unit **9051a** is adhered to the surface of this indentation **9540a** while being fitted into this indentation **9540a**. Moreover, the memory unit **9051a** is provided at an end portion in the longitudinal direction of the black developing unit **9051**. As shown in FIG. 131, this end portion is the end portion that is positioned on the downstream side with respect to the direction in which the black developing unit **9051** is inserted into the printer main unit **9010a**.

The configuration of the memory unit **9051a** is explained in detail further below.

Furthermore, a label **9580** is stuck to the housing **9540**. This label **9580** is made of PET film, and various sorts of information relating to the black developing unit **9051** are written on this label **9580**.

As shown in FIG. 131 and FIG. 132, this label **9580** is stuck to the surface of the housing **9540**, from a center portion in the longitudinal direction of the black developing unit **9051** to the end portion that is positioned on the downstream side with respect to the insertion direction, covering the memory unit **9051a**. Furthermore, as noted above, the memory unit **9051a** is adhered to the surface of the indentation **9540a**, but as shown in FIG. 134, the maximum thickness t of the memory unit **9051a** is smaller than the minimum depth d of the inden-

tation 9540a. Therefore, the label 9580 is adhered to a portion 9540b outside of the indentation (that is, a portion of the housing 9540 located around the indentation 9540a), without being adhered (stuck) to the indentation 9540a. Moreover, as shown in FIG. 134, an air layer 9590 is formed between the rear surface of the label 9580, or more specifically, that part of the rear surface of the label 9580 that is not adhered to the housing 9540, and the surface 9574 of the memory unit 9051a that is on the side opposite to the adhesive surface 9572.

It should be noted that the information written on the label 9580 is described in detail further below. Moreover, there is a protruding portion (protrusion 9576) formed on the memory unit 9051a shown in FIG. 134, and this protrusion 9576 is where a later-described non-contact IC chip 9051b of the memory unit 9051a protrudes.

In the black developing unit 9051 configured in this manner, the toner supply roller 9550 supplies the toner T contained in the toner containing member 9530 to the developing roller 9510. As the developing roller 9510 rotates, the toner T that is supplied to the developing roller 9510 is brought to the contact position of the regulating blade 9560, and when it passes that contact position, the layer thickness of the toner T is regulated, and a charge is applied to it. The toner T on the developing roller 9510, whose layer thickness has been regulated, is brought to the developing position in opposition to the photoconductor 9020 due to further rotation of the developing roller 9510 and is supplied for developing the latent image formed on the photoconductor 9020 in an alternating electric field at the developing position. The toner T on the developing roller 9510 that has passed the developing position due to further rotation of the developing roller 9510 passes the sealing member 9520 and is collected in the developing unit without being scraped off by the sealing member 9520.

<<<Configuration of the Memory Unit>>>

The configuration of the memory unit 9051a is described next, with reference to FIG. 135 and FIG. 136. FIG. 135 is a plan view showing the configuration of the memory unit 9051a. FIG. 136 is a block diagram illustrating the internal configuration of the memory unit 9051a.

The memory units with which the developing units besides the black developing unit 9051 are provided are the same as the memory unit 9051a provided on the black developing unit 9051, so that in the following description, the memory unit 9051a provided on the black developing unit 9051 is taken as an example.

The memory unit 9051a includes a thin plate-shaped substrate 9051i serving as a substrate made of a thin plate-shaped piece of plastic that is flexible in its longitudinal direction, an antenna 9051d made by arranging copper foil in a rectangular planar coil shape, antenna terminals 9051j provided on both end portions of the antenna, a non-contact IC chip 9051b including a memory and serving as an element, two coupling sections 9051k made of aluminum that connect the chip terminals of the non-contact IC chip 9051b with the antenna terminals 9051j, and a film-shaped protective sheet 9051m covering these elements, sandwiching them together with 9051i.

As shown in FIG. 135, one antenna terminal 9051j of the antenna is arranged at one end portion side in the longitudinal direction of the rectangular thin plate-shaped substrate 9051i, and the antenna is wrapped about ten times in a coil shape along the outer shape of the thin plate-shaped substrate 9051i, and the other antenna terminal 9051j is provided to the inner side of the antenna 9051d. The outer antenna terminal 9051j and the inner antenna terminal 9051j are both provided on the

same side in the longitudinal direction of the thin plate-shaped substrate 9051i. On the thin plate-shaped substrate 9051i, the ten copper foil structures of the antenna 9051d are lined up next to each other along the vertical and horizontal edges of the rectangular shape, and are divided into five each at one corner portion on that end portion side of the thin plate-shaped substrate 9051i where the antenna terminals 9051j are provided, the non-contact IC chip 9051b being arranged between these. Furthermore, two coupling sections 9051k connecting chip terminals (not shown in the drawings) provided on the non-contact IC chip 9051b with the antenna terminals 9051j are provided, respectively straddling five copper foil structures. That is to say, on the thin plate-shaped substrate 9051i, the non-contact IC chip 9051b, two antenna terminals 9051j and two coupling sections 9051k are provided on a one end side in the longitudinal direction, and the copper foil structures serving as the antenna 9051d are guided around the remaining region, except for the center.

As shown in FIG. 136, the non-contact IC chip 9051b includes a resonance capacitor 9051c, a rectifier 9051e, a signal analysis section RF (Radio Frequency) 9051f, a controller 9051g, and the memory cell 9051h. The memory cell 9051h is a nonvolatile memory that can be electrically read and written, such as an NAND flash ROM, and is capable of storing information that has been written on it and reading stored information from the outside.

The antenna 9051d of the memory unit 9051a and the main unit-side antenna 9124b for the developing unit wirelessly communicate with one another and can read information stored on the memory cell 9051h and write information to the memory cell 9051h. Also, the high frequency signals that are generated by the send-receive circuit 9123 of the printer main unit 9010a are induced as a high-frequency magnetic field via the main unit side antenna 9124b. This high-frequency magnetic field is absorbed via the antenna 9051d of the memory unit 9051a and is rectified by the rectifier 9051e, thus serving as a DC power source for driving the circuits in the non-contact IC chip 9051b.

<<<The Information Written on the Label>>>

Referring to FIG. 137, the following is an explanation of the information written on the label 9580. FIG. 137 is a diagram showing an example of the label 9580.

As shown in FIG. 137, information representing warning messages relating to the handling of the black developing unit 9051 is written on the label 9580. In the present embodiment, the information that it is forbidden to touch the developing roller 9510 is written at the position marked by symbol "A4" and the information that it is forbidden to throw the black developing unit 9051 into fire is written at the position marked by symbol "B4". Furthermore, information indicating the insertion direction of the black developing unit 9051 is written at the position marked by symbol "C4". Also, information that cautions persons handling the black developing unit 9051 to heed these warnings is written at the position marked by symbol "D4".

Furthermore, information indicating the supplier of the black developing unit 9051 (at "E4") and information indicating the color (here, black) of the toner inside the developing unit (at "F4") is written on the label 9580. It should be noted that in the present embodiment, the supplier is represented by a mark (a sun mark), but the supplier may also be expressed by text.

====Overview of the Rotary====

Next, an overview of the rotary 9055 is given using FIG. 138A, FIG. 138B, and FIG. 138C. The rotary 9055 includes a central shaft 9055a positioned in its center. A support frame

9055f for holding the developing units is fixed to this central shaft 9055a. The central shaft 9055a spans the distance between two frame side plates (not shown in the drawings) of the housing of the printer 9010, which support its two end portions. It should be noted that the axial direction of the central shaft 9055a intersects with the vertical direction.

The support frame 9055f includes four mounting and dismounting sections at spacings of 90° in circumferential direction, in which the above-mentioned four developing units 9051, 9052, 9053, and 9054 are held in a mountable and dismountable manner.

A pulse motor not shown in the drawings is connected via a clutch to the central shaft 9055a, and by driving this pulse motor, the support frame 9055f is rotated and the four developing units 9051, 9052, 9053, and 9054 can be positioned at predetermined positions.

FIG. 138A, FIG. 138B, and FIG. 138C illustrate three stop positions of the rotating rotary 9055. FIG. 138A shows a stand-by position in which the rotary 9055 is waits for the carrying out of image formation. This stand-by position is a home position (referred to as "HP position" below), which is also the stop position serving as a reference position for the rotational direction of the rotary 9055. FIG. 138B shows the communication position of the yellow developing unit 9054 mounted to the rotary 9055. FIG. 138C shows the mounting and dismounting position of the yellow developing unit 9054.

Here, in FIG. 138B and FIG. 138C, the communication position and the mounting and dismounting position of the yellow developing unit 9054 are shown, but the communication position and the mounting and dismounting position of each developing unit can be achieved by rotating the rotary 9055 successively by amounts of 90°.

First, the HP position shown in FIG. 138A is explained. An HP detection section (not shown in the drawings) for detecting the HP position is provided at one end side of the central shaft 9055a of the rotary 9055. This HP detection section includes a circular disk for generating a signal that is attached to one end of the central shaft 9055a, and an HP sensor made of a photo-interrupter including a light-emitting section and a light-receiving section. The outer edge portion of the circular disk is arranged such that it is positioned between the light-emitting section and the light-receiving section of the HP sensor. When slit sections formed in the circular disk are moved to a detection position of the HP sensor, the signal that is output by the HP sensor changes from "L" to "H". Then, the HP position of the rotary 9055 is detected from this change in signal level and the pulse number of the pulse motor, and taking this HP position as a reference, it is possible to position each of the developing units at the communication position or the like.

FIG. 138B shows the communication position of the yellow developing unit 9054, which is achieved by letting the pulse motor rotate by a predetermined number of pulses from the HP position. In the communication position of the yellow developing unit 9054 shown in FIG. 138B, the memory unit 9054a of the yellow developing unit 9054 communicates wirelessly with the main unit-side antenna 9124b for the developing unit provided on the printer main unit 9010a. It should be noted that the communication position for the yellow developing unit 9054 is the developing position of the black developing unit 9051, in which the developing roller 9510 of the black developing unit 9051 and the photoconductor 9020 face each other. That is to say, the communication position of the rotary 9055 for the yellow developing unit 9054 is the developing position of the rotary 9055 for the black developing unit 9051. Moreover, when the pulse motor rotates the rotary 9055 for 90° in the counterclockwise direc-

tion, the communication position of the black developing unit 9051 and the developing position of the cyan developing unit 9053 are attained. When the rotary 9055 is rotated by amounts of 90° each, the communication position and the developing position of each of the developing units are successively achieved.

Moreover, one of the two frame side plates that support the rotary 9055 and are part of the housing of the printer 9010 is provided with the above-mentioned developing unit mounting and dismounting opening 9010e. This developing unit mounting and dismounting opening 9010e is formed at such a position that, when the rotary 9055 is rotated and stopped at one of the mounting and dismounting positions that are set for of the developing units, only the corresponding developing unit (here, the yellow developing unit 9054) can be removed by pulling it out in a direction parallel to the central shaft 9055a, as shown in FIG. 138C. Furthermore, the developing unit mounting and dismounting opening 9010e is formed slightly larger than the outer shape of the developing unit, and in the mounting and dismounting position, it is not only possible to remove the developing unit, but also to insert a new developing unit through this developing unit mounting and dismounting opening 9010e in the direction parallel to the central shaft 9055a and mount this developing unit to the support frame 9055f. While the rotary 9055 is not positioned in a mounting and dismounting position, the mounting and dismounting of developing units is prevented by the frame side plates.

It should be noted that the rotary 9055 is provided with a locking mechanism not shown in the drawings, in order to position and fix the rotary 9055 reliably at the above-noted positions.

Advantageous Effects of the Developing Units ETC.

According to the Present Embodiment

As noted in the explanations regarding the object to be solved by the invention, the aspect of preventing destruction of the memory units 9051a, 9052a, 9053a, and 9054a has been taken into consideration in determining the positions at which the memory units 9051a, 9052a, 9053a, and 9054a are attached to the developing units 9051, 9052, 9053, and 9054. The developing units 9051, 9052, 9053, and 9054 are mounted and dismounted by a user or the like, so that it is necessary to employ countermeasures to effectively prevent the destruction of the memory units 9051a, 9052a, 9053a, and 9054a by the user touching the memory units 9051a, 9052a, 9053a, and 9054a or the memory units 9051a, 9052a, 9053a, and 9054a coming into contact with other members of the printer 9010 during the mounting or dismounting.

As an approach for solving this problem, it is known to embed the memory units 9051a, 9052a, 9053a, and 9054a in the developing units 9051, 9052, 9053, and 9054 and place a lid on them. However in this case, it is necessary to provide a separate lid, so that the number of parts increases.

By contrast, the developing units 9051, 9052, 9053, and 9054 of the present embodiment have a label 9580 on which the information regarding the developing units 9051, 9052, 9053, and 9054 is written and that is stuck to the developing units 9051, 9052, 9053, and 9054 such that it covers the memory units 9051a, 9052a, 9053a, and 9054a. That is to say, in the present embodiment, the label 9580 not only has the function of providing the person handling the developing units 9051, 9052, 9053, and 9054 (that is, the user or the like) with information regarding these developing units 9051, 9052, 9053, and 9054, but also the function of protecting the memory units 9051a, 9052a, 9053a, and 9054a by covering

them, so that it is not necessary anymore to provide a separate lid mentioned above. Consequently, with the present embodiment, it is possible to effectively prevent the destruction of memory units 9051a, 9052a, 9053a, and 9054a without increasing the number of parts.

Other Embodiments

A developing unit or the like according to the present invention was explained by way of the foregoing embodiment, but the foregoing embodiment of the invention is merely for the purpose of elucidating the present invention and is not to be interpreted as limiting the present invention. The invention can of course be altered and improved without departing from the gist thereof and equivalents are intended to be embraced therein.

In the foregoing embodiment, an intermediate image transfer type full-color laser beam printer was described as an example of the image forming apparatus, but the present invention can also be applied to various other types of image forming apparatuses, such as full-color laser beam printers that are not of the intermediate image transfer type, monochrome laser beam printers, copying machines, and facsimiles.

Also the memory units 9051a, 9052a, 9053a, and 9054a are not limited to the configuration explained in this embodiment. For example, they may also be devised such that the antenna 9051d is provided separately. Moreover, in the foregoing embodiment, the memory units 9051a, 9052a, 9053a, and 9054a are capable of communication wirelessly with the printer main unit 9010a in a state in which the developing units 9051, 9052, 9053, and 9054 are mounted to the printer main unit 9010a, but there is no limitation to this.

Moreover, in the foregoing embodiment, the memory units 9051a, 9052a, 9053a, and 9054a are arranged on the downstream side with respect to the insertion direction of the developing units 9051, 9052, 9053, and 9054, but there is not limitation to this. For example, it is also possible to arrange the memory units 9051a, 9052a, 9053a, and 9054a on the upstream side with respect to the insertion direction of the developing units 9051, 9052, 9053, and 9054.

However, the foregoing embodiment is more preferable in view of the fact that the memory units 9051a, 9052a, 9053a, and 9054a are more difficult to touch by the user during the mounting and dismounting of the developing units 9051, 9052, 9053, and 9054 with respect to the printer main unit 9010a, so that it is possible to prevent the destruction of the memory units 9051a, 9052a, 9053a, and 9054a more effectively.

Moreover, in the foregoing embodiment, the memory units 9051a, 9052a, 9053a, and 9054a are provided on the housing 9540 of the developing units 9051, 9052, 9053, and 9054, and the label 9580 is stuck to the surface of the housing 9540 in such a manner that it covers the memory units 9051a, 9052a, 9053a, and 9054a, but there is not limitation to this. For example, it is also possible to provide the memory units 9051a, 9052a, 9053a, and 9054a at a portion other than the housing 9540. It is also possible to stick the label 9580 to a portion other than the housing 9540.

Furthermore, in the foregoing embodiment, the memory units 9051a, 9052a, 9053a, and 9054a are stuck to the surface of the housing 9540, but there is no limitation to this. For example, it is also possible to fix the memory units 9051a, 9052a, 9053a, and 9054a to the housing 9540 with screws.

However, the foregoing embodiment is more effective not only due to the fact that the label 9580 has the above-described effect of effectively preventing the destruction of the

memory units 9051a, 9052a, 9053a, and 9054a without increasing the number of parts, but also with regard to the effect of effectively preventing, without increasing the number of parts, that the memory units 9051a, 9052a, 9053a, and 9054a are peeled off from the housing 9540 by toner intruding between the rear side of the memory units 9051a, 9052a, 9053a, and 9054a and the surface of the housing 9540.

Furthermore, in the foregoing embodiment, the housing 9540 has an indentation 9540a, the memory units 9051a, 9052a, 9053a, and 9054a are adhered to the surface of the indentation 9540a, and the label 9580 is stuck to a portion 9540b of the housing 9540 that is not the indentation, but there is no limitation to this. For example, it is also possible that the housing 9540 does not have an indentation 9540a.

However, the foregoing embodiment is more preferable in view of the fact that the memory units 9051a, 9052a, 9053a, and 9054a are more difficult to touch by the user if the memory units 9051a, 9052a, 9053a and 9054a are accommodated in such indentations 9540a, so that it is possible to prevent the destruction of the memory units 9051a, 9052a, 9053a, and 9054a more effectively.

Moreover, in the foregoing embodiment, the maximum thickness of the memory units 9051a, 9052a, 9053a, and 9054a is smaller than the minimum depth of the indentation 9540a, but there is no limitation to this. For example, it is also possible to let the maximum thickness of the memory units 9051a, 9052a, 9053a, and 9054a be larger than the minimum depth of the indentation 9540a.

However, the foregoing embodiment is more preferable in view of the fact that the memory units 9051a, 9052a, 9053a, and 9054a are more difficult to touch by the user if the memory units 9051a, 9052a, 9053a, and 9054a are accommodated entirely in such indentations 9540a, so that it is possible to prevent the destruction of the memory units 9051a, 9052a, 9053a, and 9054a more effectively.

Moreover, in the foregoing embodiment, an air layer 9590 is formed between the rear side of the label 9580 and the surface 9574 of the memory units 9051a, 9052a, 9053a, and 9054a that is on the opposite side of the adhesive surface 9572, but there is no limitation to this. For example, it is also possible to stick the label 9580 to the front surface 9574 of the memory units 9051a, 9052a, 9053a, and 9054a, so that no air layer 9590 is formed.

However, the foregoing embodiment is preferable with regard to the fact that the air layer 9590 has the cushioning function of suitably preventing the destruction of the memory units 9051a, 9052a, 9053a and 9054a even if the user presses the label 9580.

Moreover, as shown in FIG. 139, it is also possible that the developing units 9051, 9052, 9053 and 9054 have a cushion material 9595 between the surface 9574 of the memory units 9051a, 9052a, 9053a and 9054a that is on the opposite side of the adhesive surface 9572 and the rear surface of the label 9580.

In this case, the cushion material 9595 fulfills the function of a cushion and suitably prevents the destruction of the memory units 9051a, 9052a, 9053a, and 9054a even when the user pushes down the label 9580. It should be noted that FIG. 139 corresponds to FIG. 134 and is a cross-sectional diagrammatic view showing the cushion material 9595.

Moreover, in the foregoing embodiment, information representing warning messages relating to the handling of the developing units, information cautioning the persons handling the developing units, information indicating the supplier of the developing unit, information indicating the toner color, and information indicating the insertion direction of the developing unit were given as examples of the information

199

relating to the developing units that is written onto the labels **9580** that are stuck to the developing units **9051**, **9052**, **9053** and **9054** such that they cover the memory units **9051a**, **9052a**, **9053a** and **9054a**. However, there is no limitation to this, and it may be any information relating to the developing unit.

Moreover, as shown in FIG. 140, as information relating to the developing units, it is also possible to write onto the label **9580** the information that persons handling the developing unit must not grasp the developing unit at the portion where the label is stuck.

In this case, the possibility that persons handling the developing unit, such as users, touch the memory units **9051a**, **9052a**, **9053a**, and **9054a** is reduced, and it becomes possible to prevent the destruction of the memory units **9051a**, **9052a**, **9053a**, and **9054a** more effectively. FIG. 140 is a diagram showing an example of information indicating the fact that persons handling the developing unit must not grasp the developing unit at the portion where the label is stuck.

As shown in FIG. 141, it is also possible that information urging persons handling the developing unit to grasp the developing unit at a portion other than the portion where the label is stuck is written on the label **9580** or that other portion.

Also in this case, the possibility that persons handling the developing unit touch the memory units **9051a**, **9052a**, **9053a**, and **9054a** is reduced, and it becomes possible to prevent the destruction of the memory units **9051a**, **9052a**, **9053a**, and **9054a** more effectively. FIG. 141 is a diagram showing an example of such information urging persons handling the developing unit to grasp the developing unit at a portion other than the portion where the label is stuck.

Moreover, in the foregoing, an example is given in which the present invention is applied to developing units **9051**, **9052**, **9053**, and **9054**, but it is also possible to apply the present invention to the photoconductor unit **9075**. As noted above, a memory unit **9075a** is provided on the photoconductor unit **9075**. This memory unit **9075a** has, for example, the above-described configuration, that is, the configuration shown in FIG. 135 and FIG. 136. As shown in FIG. 142, a label **9075c** on which information relating to the photoconductor unit **9075** is written may be stuck to the housing **9075b** of the photoconductor unit **9075**, covering the memory unit **9075a**. FIG. 142 is an exploded perspective view showing the positional relationship between the housing **9075b**, the memory unit **9075a**, and the label **9075c** of the photoconductor unit **9075**.

==Configuration of Image Forming System Etc.==

Next, an embodiment of an image forming system serving as an example of an embodiment of the present invention is described with reference to the drawings.

FIG. 143 is an explanatory diagram showing the external configuration of an image forming system. An image forming system **9700** is provided with a computer **9702**, a display device **9704**, a printer **9706**, input devices **9708**, and reading devices **9710**. In this embodiment, the computer **9702** is contained within a mini-tower type housing, but there is no limitation to this. A CRT (cathode ray tube), plasma display, or liquid crystal display device, for example, is generally used as the display device **9704**, but there is no limitation to this. As the printer **9706**, the printer described above is used. In this embodiment, the input devices **9708** are a keyboard **99708A** and a mouse **9708B**, but there is no limitation to these. In this embodiment, a flexible disk drive device **9710A** and a CD-ROM drive device **9710B** are used as the reading devices **9710**, but the reading devices **9710** are not limited to these,

200

and may also include an MO (magneto-optical) disk drive device or a DVD (digital versatile disk), for example.

FIG. 144 is a block diagram showing the configuration of the image forming system shown in FIG. 143. An internal memory **9802** such as a RAM is provided within the casing containing the computer **9702**, and furthermore an external memory such as a hard disk drive unit **9804** is provided.

In the above explanations, an example was given in which the image forming system is constituted by connecting the printer **9706** to the computer **9702**, the display device **9704**, the input devices **9708**, and the reading devices **9710**, but there is no limitation to this. For example, the image forming system may also be made of the computer **9702** and the printer **9706**, and the image forming system does not have to be provided with any one of the display device **9704**, the input devices **9708**, and the reading devices **9710**.

It is also possible that the printer **9706** has some of the functions or mechanisms of the computer **9702**, the display device **9704**, the input devices **9708**, and the reading devices **9710**. For example, the printer **9706** may be configured so as to have an image processing section for carrying out image processing, a display section for carrying out various types of displays, and a recording media mounting and dismounting section into and from which recording media storing image data captured by a digital camera or the like are inserted and taken out.

As an overall system, the image forming system that is thus achieved is superior to conventional systems.

The invention claimed is:

1. A developing device that can be mounted to and dismounted from a mounting and dismounting section provided in an image forming apparatus main unit, the developing device comprising:
  - a developing device main unit;
  - a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit;
  - a coupling member that is to be coupled to the mounting and dismounting section when the developing device is mounted to the mounting and dismounting section, the coupling member being attached to the other end side in the longitudinal direction of the developing device main unit in such a manner that its relative position to the developing device main unit can be changed; and
  - an element capable of communication in a noncontacting manner with the image forming apparatus main unit side when the developing device is mounted to the mounting and dismounting section, the element being provided at the one end side in the longitudinal direction of the developing device main unit.
2. A developing device according to claim 1, wherein the mounting and dismounting section is movable; wherein the developing device develops a latent image borne on an image bearing member with which the image forming apparatus main unit is provided, when having been moved to a first position through a movement of the mounting and dismounting section while being mounted to the mounting and dismounting section; and wherein the element communicates in a noncontacting manner with the image forming apparatus main unit side

201

- when the developing device has been moved to a second position that is different from the first position.
3. A developing device according to claim 2, wherein the mounting and dismounting section includes a spring that biases the developing device main unit along its longitudinal direction; and the relative position of the developing device main unit and the coupling member changes in accordance with the biasing amount provided by the spring.
4. A developing device according to claim 2, wherein the developing device main unit includes:
- a developer bearing member that bears a developer, and that is for developing the latent image borne on the image bearing member with the developer; and
  - a distance holding member for holding a distance between the image bearing member and the developer bearing member by coming into contact with the image bearing member, the distance holding member being provided on both end portions in a longitudinal direction of the developer bearing member;
- wherein the distance holding member holds the distance by coming into contact with the image bearing member when the developing device has moved to the first position.
5. A developing device according to claim 1, wherein the developing device main unit is provided with an attachment protrusion having a circular cross section; wherein the coupling member is provided with an attachment hole that has an elliptical cross section and into which the attachment protrusion can be fitted; and wherein the attachment hole allows movement, within the attachment hole, of the attachment protrusion fitted into the attachment hole.
6. A developing device according to claim 1, wherein the developing device main unit is provided with a housing for containing a developer; and wherein the element is attached to an outer surface of the housing, the outer surface extending along a longitudinal direction of the housing.
7. A developing device according to claim 6, wherein the developing device main unit includes a developer bearing member that is supported by the housing at both end portions in its longitudinal direction, and that is for bearing a developer and developing a latent image borne on the image bearing member with the developer; wherein the outer surface of the housing includes a circularly arc-shaped surface whose cross section through a perpendicular plane that is perpendicular to the longitudinal direction of the housing is circularly arc-shaped; and wherein the element is attached to a position of the circularly arc-shaped surface that is furthest removed from the developer bearing member.
8. A developing device according to claim 1 further comprising:
- an element that, when the developing device is mounted to the image forming apparatus main unit, faces, across a gap, an antenna provided to the image forming apparatus main unit, and is capable of wireless communication with the antenna; and
  - a metal plate, at least a portion of which is positioned to the outer side of the gap and at a position corresponding to the gap in a direction from the element toward the antenna, when the developing device is mounted to the image forming apparatus main unit and the element performs wireless communication with the antenna.

202

9. A developing device according to claim 8, comprising: a developer bearing roller provided extending along a longitudinal direction of the developing device, that is for bearing a developer;
- a first driving wheel provided at one end portion of the developer bearing roller, that is for driving the developer bearing roller; and
  - a second driving wheel that receives a driving force from the image forming apparatus main unit when the developing device is mounted to the image forming apparatus main unit, and that transmits the driving force to the first driving wheel;
- wherein the metal plate is a positioning member for positioning the first driving wheel and the second driving wheel.
10. A developing device according to claim 9, wherein the element is provided at an end portion, in the longitudinal direction of the developing device, at which the first driving wheel is positioned.
11. An image forming system according to claim 1 further comprising:
- wherein the image forming apparatus main unit includes an antenna; and
  - the developing device includes: an element that, when the developing device is mounted to the image forming apparatus main unit, faces the antenna across the gap, and is capable of wireless communication with the antenna; and a metal plate, at least a portion of which is positioned to the outer side of the gap and at a position corresponding to the gap in a direction from the element toward the antenna, when the developing device is mounted to the image forming apparatus main unit and the element performs wireless communication with the antenna.
12. A developing device according to claim 1, further comprising:
- a cartridge comprising:
  - a communication unit including:
  - a base;
  - an antenna supported by the base; and
  - an element supported by the base, the element being for communication via the antenna; and
  - (b) a housing by which the communication unit is supported with the element being positioned on an upstream side of the base, with respect to a mounting direction in which it is mounted to the image forming apparatus main unit.
13. A developing device according to claim 12, wherein the communication unit communicates with the image forming apparatus main unit via an apparatus-side antenna provided to the image forming apparatus main unit.
14. A developing device according to claim 12, comprising a positioning section for positioning with respect to the image forming apparatus main unit on a downstream side in the mounting direction, wherein the communication unit is arranged on the downstream side in the mounting direction.
15. A developing device according to claim 12, wherein the base is fixed to the housing, and wherein the antenna and the element are supported by the base on the side of the base that is opposite to the housing and are covered by a film.

203

16. A developing device according to claim 12, wherein the image forming apparatus main unit includes: an opening through which the cartridge is inserted; and a guiding portion that guides the cartridge to a mounting position; wherein the element is passed through the opening and mounted after the guiding portion has been engaged when introducing the cartridge from the opening.

17. A developing device according to claim 1, further comprising:

a developing container containing a developer including a magnetic material; a container-side antenna provided at the developing container, that is for communicating in a contactless manner, when mounted to an apparatus main unit, with a main unit-side antenna of the apparatus main unit; and an intrusion prevention section for preventing intrusion of the developer into a predetermined region between the container-side antenna and the developer.

18. A developing device according to claim 17, wherein the intrusion prevention section is a partitioning member for forming a gap by partitioning the predetermined region.

19. A developing device according to claim 17, wherein the intrusion prevention member is a region holding member that is provided such that it fills out the predetermined region.

20. A developing device according to claim 19, wherein the region holding member is a block made of urethane.

21. A developing device according to claim 17, wherein the container-side antenna and the main unit-side antenna communicate at positions spaced apart by a distance L; and

wherein the predetermined region includes a region of a distance L from the container-side antenna, and is wider than that region.

22. A developing unit as claimed in claim 1, further comprising:

a memory unit including a memory; and a label on which information relating to the developing unit is written, and that has been stuck to the developing unit so as to cover the memory unit.

23. A developing unit according to claim 22, wherein the memory unit can communicate wirelessly with the image forming apparatus main unit side, when the developing unit is mounted to the image forming apparatus main unit.

24. A developing unit according to claim 22, wherein the developing unit is mounted to the image forming apparatus main unit by inserting it into the image forming apparatus main unit; and

wherein the memory unit is provided on a downstream side, with respect to the insertion direction, of the developing unit.

25. A developing unit according to claim 22, wherein the memory unit is provided on a housing of the developing unit; and

wherein the label has been stuck to a surface of the housing so as to cover the memory unit.

26. A developing unit according to claim 25, wherein the memory unit is adhered to a surface of the housing.

204

27. A developing unit according to claim 26, wherein the housing includes an indentation; wherein the memory unit is adhered to a surface of the indentation; and

5 wherein the label has been stuck to a portion of the housing outside of the indentation.

28. A developing unit according to claim 27, wherein a maximum thickness of the memory unit is smaller than a minimum depth of the indentation.

10 29. A developing unit according to claim 27, wherein an air layer is formed between a rear surface of the label and a surface of the memory unit on the side opposite to the adhesive surface.

15 30. A developing unit according to claim 27, comprising a cushion material between a rear surface of the label and a surface of the memory unit on the side opposite to the adhesive surface.

31. A developing unit according to claim 22, wherein the information is information representing warning messages relating to the handling of that developing unit.

20 32. A developing unit according to claim 22, wherein the information is information cautioning persons handling that developing unit.

33. A developing unit according to claim 22, wherein the information is information indicating a supplier of that developing unit.

34. A developing unit according to claim 22, wherein a developer is contained in the developing unit; and

wherein the information is information indicating the color of the developer.

35. A developing unit according to claim 22, wherein the developing unit is mounted to the image forming apparatus main unit by insertion into the image forming apparatus main unit; and wherein the information is information indicating an inserting direction of the developing unit.

36. A developing unit according to claim 22, wherein the information is information indicating that persons handling the developing unit must not grasp the developing unit at a portion to which the label has been stuck.

37. A developing unit according to claim 22, wherein information is written that urges a person handling the developing unit to grasp the developing unit at a portion other than the portion to which the label has been stuck.

38. An image forming apparatus comprising: an image bearing member for bearing a latent image; and a developing device that can be mounted to and dismounted from a mounting and dismounting section provided in an image forming apparatus main unit, the developing device including: a developing device main unit; a positioning member for positioning the developing device main unit with respect to the mounting and dismounting section by engaging the mounting and dismounting section when the developing device is mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in a longitudinal direction of the developing device main unit in such a manner that its relative position to the

205

developing device main unit can be changed; and an element capable of communication in a noncontacting manner with the image forming apparatus main unit side when the developing device is mounted to the mounting and dismounting section, the element being provided at the one end side in the longitudinal direction of the developing device main unit, the developing device being for developing a latent image borne on the image bearing member when being mounted to the mounting and dismounting section.

39. An image forming apparatus according to claim 38, further comprising:

a developing cartridge for developing the latent image by selectively adhering a toner to the latent image on a surface of the bearing member;
a developing rotary unit provided in the apparatus main unit, that accommodates a plurality of the developing cartridges that can be inserted and removed around a rotation shaft, and lets one of the developing cartridges oppose the surface of the bearing member by rotating around the rotation shaft; and
a storage element that stores and holds information relating to the developing cartridge, the storage element being provided at a position on an outer surface of the developing cartridge where its distance to an external cover of the apparatus main unit is shortest when the memory element communicates with the apparatus main unit after having been stopped in that stop position of the plurality of stop positions, at which the developing cartridge stops when being rotatively moved by the developing rotary unit, in which the outer surface of the developing cartridge is closest to the external cover.

40. An image forming apparatus according to claim 39, wherein, in the position in which the apparatus main unit communicates with the storage element, the storage element is positioned in a region in which it is furthest removed from a heat-generating member within the apparatus main unit.

41. An image forming apparatus according to claim 39, wherein the external cover is provided with a vent hole near the position in which the apparatus main unit communicates with the storage element.

42. An image forming apparatus according to claim 39, further comprising, in the position in which the apparatus main unit communicates with the storage element, a ventilation means that blows air onto a member surface near the storage element by forcibly generating an air-flow near the storage element.

43. An image forming apparatus according to claim 42, further comprising an exhaust duct that is provided with a drainage opening near the storage element at the position in which the apparatus main unit communicates with the storage element and that is for sucking air inside the apparatus main unit and exhausting it out of the apparatus;

wherein the ventilation means forcibly generates the air-flow near the storage element by sucking air into the exhaust duct.

44. An image forming apparatus according to claim 39, wherein antennas are provided at positions where the developing cartridge side faces the apparatus main unit side, allowing the storage element and the apparatus main unit to communicate in a noncontacting manner, and the antenna on the developing cartridge side is adjacent to the storage element.

45. An image forming apparatus comprising according to claim 39, wherein:

206

the image forming apparatus main unit includes an antenna; and

the developing device includes: an element that, when the developing device is mounted to the image forming apparatus main unit, faces the antenna across a gap, and is capable of wireless communication with the antenna; and a metal plate, at least a portion of which is positioned to the outer side of the gap and at a position corresponding to the gap in a direction from the element toward the antenna, when the developing device is mounted to the image forming apparatus main unit and the element performs wireless communication with the antenna.

46. An image forming apparatus according to claim 45, wherein the image forming apparatus main unit includes a rotatable rotating member including a mounting and dismounting section to which the developing device can be mounted and dismounted;

wherein the element performs wireless communication with the antenna, when the developing device has been rotated through rotation of the rotating member with the developing device mounted in the mounting and dismounting section, so that the element provided on the developing device faces the antenna across the gap.

47. An image forming apparatus according to claim 45, wherein the developing device includes:

a developer bearing roller for bearing a developer, that is provided extending along a longitudinal direction of the developing device;

a first driving wheel for driving the developer bearing roller, that is provided at a one end portion of the developer bearing roller; and

a second driving wheel that receives a driving force from the image forming apparatus main unit when the developing device is mounted to the image forming apparatus main unit, and that is for transmitting the driving force to the first driving wheel;

wherein the metal plate is a positioning member for positioning the first driving wheel and the second driving wheel.

48. An image forming apparatus according to claim 47, wherein the element is provided at an end portion, in a longitudinal direction of the developing device, at which the first driving wheel is positioned.

49. An image forming apparatus according to claim 45, wherein the image forming apparatus main unit includes a motor; and

wherein the metal plate is positioned between the motor and the gap when the element communicates wirelessly with the antenna.

50. An image forming apparatus according to claim 45, wherein the image forming apparatus main unit includes: a main unit-side metal plate at least a portion of which is positioned to an outer side of the gap and at a position corresponding to the gap in a direction from the element toward the antenna, when the element communicates wirelessly with the antenna.

51. An image forming apparatus according to claim 38, further comprising:

a developing cartridge for developing the latent image by selectively adhering a toner to the latent image on a surface of the bearing member;

a developing rotary unit provided in the apparatus main unit, that accommodates a plurality of the developing cartridges that can be inserted and removed around a rotation shaft, and lets one of the developing cartridges oppose the surface of the bearing member by rotating around the rotation shaft;

207

a duct having a suction opening for sucking a toner that drifts in a vicinity of a developing position at which the developing cartridge adheres a toner to the latent image on the surface of the developing member, by providing suction near the developing position; and
 a storage element capable of communication with the apparatus main unit, that stores and holds information relating to the developing cartridge, the storage element being provided on an outer surface of the developing cartridge to the outside of a region facing a part of the duct where the suction opening is formed, when the developing cartridge is rotated and passes the vicinity of the suction opening.

52. An image forming apparatus according to claim 51, wherein the storage element and the apparatus main unit 15 include communication sections for communicating; wherein antennas are placed at positions where the developing cartridge side faces the apparatus main unit side, so that the communication sections have a function of performing communication in a noncontacting manner, and the antenna on the developing cartridge side is adjacent to the apparatus element.

53. An image forming apparatus according to claim 38, further comprising:

a developing cartridge for developing the latent image by 25 selectively adhering toner to the latent image on a surface of the bearing member;
 a developing rotary unit provided in an apparatus main unit, that accommodates a plurality of the developing cartridges that can be inserted and removed around a rotation shaft, and lets one of the developing cartridges oppose the surface of the bearing member by rotating around the rotation shaft;
 a duct having a suction opening for sucking a toner that drifts in a vicinity of a developing position at which the developing cartridge adheres a toner to the latent image on the surface of the developing member, by providing suction near the developing position;
 a storage element for storing and holding information relating to the developing cartridge; and
 40 communication sections for letting the apparatus main unit and the storage element communicate with each other, the communication sections being placed to the outside, in a direction along the rotation shaft, of a part of the duct where the suction opening is formed.

54. An image forming apparatus according to claim 53, wherein the communication sections include a developing cartridge-side antenna and an apparatus main unit-side antenna for letting the storage element and the apparatus main unit communicate with each other, the developing cartridge-side antenna and the apparatus main unit-side antenna facing each other outside, in a direction along the rotation shaft, of a part of the duct where the suction opening is formed, so that the storage element and the apparatus main unit perform communication in a non-contacting manner.

55. An image forming apparatus according to claim 38 that forms an image by transferring a toner image on a bearing member surface onto a recording medium and fixing the toner image, the image forming apparatus comprising:

the bearing member that bears a toner image made by forming the latent image based on image data on a surface and developing that latent image;
 an exposing unit that forms the latent image based on the image data by selectively scanning and exposing the bearing member surface;

208

a developing cartridge that develops the latent image by selectively adhering toner to the latent image on the bearing member surface;

a developing rotary unit that accommodates a plurality of the developing cartridges that can be inserted and removed around a rotation shaft and lets one of the developing cartridges face the bearing member surface by rotating around the rotation shaft; and
 a controller that controls the driving of various sections of the apparatus, including the bearing member and the developing cartridge, based on received image data and various kinds of information;

wherein a storage element storing and holding information relating to the developing cartridge is placed on an outer surface of the developing cartridge, and a communication means is provided that performs communication by reading out at least information inside the storage element as information to be processed by the controller; and

wherein the storage element is arranged outside a position facing a heat-generating member when the rotation of the developing cartridge is stopped.

56. An image forming apparatus according to claim 55, wherein the heat-generating member is a scanner motor that rotates, at high speed, within the exposing unit in order to scan laser light that exposes the bearing member surface, or a driver section that controls the driving of the scanner motor.

57. An image forming apparatus according to claim 55, wherein a communication section has a function of performing communication in a noncontacting manner, with antennas being placed at positions where the developing cartridge side faces the apparatus main unit side, and the antenna on the developing cartridge side is adjacent to the storage element.

58. An image forming apparatus according to claim 55, wherein the storage element is arranged at a position that is removed, in the rotation direction, from a position where the heat-generating member faces an outer surface of the developing cartridge whose rotation is stopped.

59. An image forming apparatus according to claim 58, wherein the developing cartridge includes a developing roller that adheres contained toner onto the bearing member surface; and

wherein also the developing roller is arranged at a position that is removed, in the rotation direction, from a position where the heat-generating member faces an outer surface of the developing cartridge whose rotation is stopped.

60. An image forming apparatus according to claim 55, wherein the storage element is arranged at a position that is removed, in an axial direction of the rotation shaft, from a position where the heat-generating member faces an outer surface of the developing cartridge whose rotation is stopped.

61. An image forming apparatus according to claim 38 that forms an image by transferring a toner image on a bearing member surface onto a recording medium and fixing the toner image, the image forming apparatus comprising: the bearing member that bears a toner image made by forming the latent image based on image data on a surface and developing that latent image; a developing cartridge that develops the latent image by selectively adhering toner to the latent image on the bearing member surface; a developing rotary unit that accommodates a plurality of the developing cartridges that can be inserted or removed around a rotation shaft and lets one of the developing cartridges face the bearing member surface by

209

rotating around the rotation shaft; a controller that controls the driving of various sections of the apparatus, including the bearing member and the developing cartridge, based on received image data and various kinds of information; the image forming apparatus further including:

a storage element that stores and holds information relating to the developing cartridge, placed on an outer surface of the developing cartridge, and a communication means that has a function of performing communication in a noncontacting manner, with antennas being placed at positions where the developing cartridge side can face the apparatus main unit side, and that performs communication in a noncontacting manner by reading out at least information inside the storage element as information processed by the controller;

wherein a blocking member is placed between a high-voltage member, which takes on a voltage equal or greater than that which is necessary for the adherence and transfer of a toner, and a rotation trajectory of the storage element on the outer surface of the developing cartridge, the blocking member limiting the influence that noise caused by the high-voltage member has on the storage element.

62. An image forming apparatus according to claim 61, wherein the storage element is placed on the outer surface of the developing cartridge, adjacent to the developing cartridge-side antenna.

63. An image forming apparatus according to claim 61, wherein the high-voltage member includes either one or both of a voltage applying member, which charges a contacting member with a high voltage, or that charged member.

64. An image forming apparatus according to claim 63, wherein the charged member is the bearing member bearing the toner image obtained by developing the latent image, and the voltage applying member is a member charging the bearing member surface to a potential at which the latent image is formed and toner is adhered.

65. An image forming apparatus according to claim 63, provided with an intermediate image transfer member that, after the toner image on the bearing member surface has been transferred to it by primary image transfer, performs secondary image transfer of the toner image onto a recording medium;

wherein the charged member is the intermediate image transfer member, and the voltage applying member is a member that charges the intermediate image transfer member to a potential at which the toner image is borne after receiving it from the bearing member.

66. An image forming apparatus according to claim 61, wherein the blocking member is placed at a position where the high-voltage member faces the antenna or the storage element.

67. An image forming apparatus according to claim 38, wherein the developing device includes the following (a) and (b):

(a) a communication unit including:
a base;
an antenna supported by the base; and
an element supported by the base, the element being for communication via the antenna; and
(b) a housing by which the communication unit, with the element being positioned on an upstream side of the base, is supported, with respect to a mounting direction in which it is mounted to the image forming apparatus main unit.

210

68. An image forming apparatus according to claim 38, further comprising:

(a) a mounting section that is to be mounted with a cartridge provided with an element unit having a first antenna and an element;

(b) an antenna unit including a second antenna for communicating with the first antenna, the antenna unit being arranged at a position that is spaced by a predetermined distance L from the first antenna of the cartridge mounted into the mounting section; and

(c) a communication region in which no conductive members are present besides the element unit, the antenna unit and a wire connected to the antenna unit, within a distance of L from the first antenna and within a distance of L from the second antenna.

69. An image forming apparatus according to claim 68, comprising a holder made of resin, the holder including a flexible tongue;

wherein the antenna unit is fixed via the holder by engaging the base supporting the second antenna with the tongue.

70. An image forming apparatus according to claim 68, comprising a metal shielding member outside of the communication region.

71. An image forming apparatus according to claim 70, wherein the shielding member is an apparatus shielding member for blocking the image forming apparatus with respect to the outside.

72. An image forming apparatus according to claim 70, comprising a power source and a power source shielding member covering the power source;

wherein the shield is used as the power source shielding member.

73. An image forming apparatus according to claim 38, wherein the developing device includes:

a developing container containing a developer including a magnetic material;

a container-side antenna provided at the developing container, that is for communicating in a contactless manner, when mounted to an apparatus main unit, with a main unit-side antenna of the apparatus main unit; and an intrusion prevention section for preventing intrusion of the developer into a predetermined region between the container-side antenna and the developer.

74. An image forming apparatus according to claim 38, further comprising:

(a) a mounting section that is to be mounted with a cartridge so that it can be mounted and dismounted;

(b) a duct serving as an air passageway within an apparatus including the mounting section; and

(c) a second antenna provided to the duct, the second antenna being for communicating with an element provided with the cartridge, via a first antenna provided to the cartridge.

75. An image forming apparatus according to claim 74, wherein the second antenna is provided inside the duct.

76. An image forming apparatus according to claim 74, wherein the second antenna is provided at an inner wall of the duct.

77. An image forming apparatus according to claim 74, wherein the second antenna is provided at an outer wall of the duct.

211

78. An image forming apparatus according to claim 74, wherein upstream, with respect to the direction of the air flow, from an antenna placement part where the second antenna is arranged, the duct has a part with a cross-sectional area that is larger than a cross-sectional area in a direction intersecting with the direction of the air flow at the antenna placement location. 5

79. An image forming apparatus according to claim 74, wherein the duct is made of resin. 10

80. An image forming apparatus according to claim 74, wherein the duct is an exhaust duct for exhausting air inside the apparatus to outside of the apparatus. 15

81. An image forming apparatus according to claim 74, wherein a filter is provided upstream of the second antenna, with respect to the direction of the air flow inside the duct. 15

82. An image forming apparatus according to claim 81, wherein a latent image borne on the image bearing member is developed using a developer; and 20 the filter is provided in order to scavenge the developer. 20

83. An image forming apparatus according to claim 82, wherein the developer is a toner. 25

84. An image forming apparatus according to claim 74, comprising an antenna driving circuit connected to the second antenna, that is for achieving communication between the first antenna and the second antenna; 30 wherein the antenna driving circuit is provided at the duct. 30

85. An image forming apparatus according to claim 38, wherein the developing unit includes: a memory unit including a memory; and a label on which information relating to the developing unit is written, and that has been stuck to the developing unit so as to cover the memory unit. 35

86. An image forming system comprising: a computer; and 40 an image forming apparatus that can be connected to the computer, the image forming apparatus including: an image bearing member for bearing a latent image; and a developing device that can be mounted to and dismounted from a mounting and dismounting section provided in an image forming apparatus main unit, the developing device including: a developing device main unit; a positioning member for positioning the developing device main unit with respect to the mounting and dismounting section by engaging the mounting and dismounting section when the developing device is 45 mounted to the mounting and dismounting section, the positioning member being fixed on a one end side in a longitudinal direction of the developing device main unit; a coupling member that is to be coupled to the mounting and dismounting section when the developing device is mounted to the mounting and dismounting section, the coupling member being attached to the other end side in a longitudinal direction of the developing device main unit in such a manner that its relative position to the developing device main unit can be changed; and an element capable of communication in a noncontacting manner with the image forming apparatus main unit side when the developing device is mounted to the mounting and dismounting section, the element being provided at the one end side in the longitudinal direction of the developing device main unit, the developing device being for developing a latent image borne on the image bearing member when being mounted to the mounting and dismounting section. 50

87. An image forming system according to claim 86, wherein the developing device includes the following (a) and (b): 55

212

(a) a communication unit including: a base; an antenna supported by the base; and an element supported by the base, the element being for communication via the antenna; and (b) a housing by which the communication unit, with the element being positioned on an upstream side of the base, is supported, with respect to a mounting direction in which it is mounted to the image forming apparatus main unit. 10

88. An image forming system according to claim 86, wherein the image forming apparatus includes the following (a) to (i): 15

(a) a mounting section that is to be mounted with a cartridge provided with an element unit including a first antenna and an element; 20

(b) an antenna unit having a second antenna for communicating with the first antenna, the antenna unit being arranged at a position that is spaced by a predetermined distance L from the first antenna of the cartridge mounted into the mounting section; 25

(c) a communication region in which no conductive member is present besides the element unit, the antenna unit and a wire connected to the antenna unit, within a distance of L from the first antenna and within a distance of L from the second antenna; 30

(d) a holder made of resin, the holder including a flexible tongue, wherein the antenna unit is fixed via the holder by engaging the base supporting the second antenna with the tongue; and 35

(e) a metal shielding member outside of the communication region; 40

(f) the shielding member being an apparatus shielding member for blocking the image forming apparatus with respect to the outside; 45

(g) a power source and a power source shielding member covering the power source, the shield being used as the power source shielding member; and 50

(h) wherein the cartridge is a developing device containing a developer for developing a latent image. 55

89. An image forming system according to claim 86, wherein the developing device includes: 60

a developing container containing a developer including a magnetic material; 65

a container-side antenna provided at the developing container, that is for communicating in a contactless manner, when mounted to an apparatus main unit, with a main unit-side antenna of the apparatus main unit; and an intrusion prevention section for preventing intrusion of the developer into a predetermined region between the container-side antenna and the developer. 70

90. An image forming system according to claim 86, wherein the image forming apparatus includes the following (a) to (c): 75

(a) a mounting section that is to be mounted with a cartridge so that it can be mounted and dismounted; 80

(b) a duct serving as an air passageway within an apparatus including the mounting section; 85

(c) a second antenna provided to the duct, the second antenna being for communicating with an element provided to the cartridge, via a first antenna provided to the cartridge. 90

91. An image forming system according to claim 86, wherein the developing unit includes: a memory unit including a memory; and a label on which information relating to the developing unit is written, and that has been stuck to the developing unit so as to cover the memory unit. 95
